UNITED STATES PATENT OFFICE.

LOUIS F. DIETER, OF BUFFALO, NEW YORK,

METHOD OF AND APPARATUS OR MILL FOR ROLLING OR FORMING CAR-WHEELS OR OTHER CIRCULAR BODIES.

1,319,142.

Specification of Letters Patent.

Patented Oct. 21, 1919.

Continuation of application Serial No. 633,343, filed June 15, 1911. This application filed October 9, 1917. Serial No. 195,637.

To all whom it may concern:

Be it known that I, LOUIS F. DIETER, a citizen of the United States, residing at Buffalo, in the county of Erie and State of New York, have invented a novel and useful Method of and Apparatus or Mill for Rolling or Forming Car-Wheels or other Circular Bodies, of which the following is a specification accompanied by fourteen sheets of drawings forming part of this specification.

The features of my invention claimed herein are related to the invention of my original application for patent filed June 15, 1911, Serial No. 633,343, Patent No. 1,243,050. 15 This application is a continuation of my said original application, and, for carrying out my invention I prefer to use an apparatus or mill such for instance as shown and described in my said original application 20 with the exception of the modifications in operations and parts thereof herein shown and described, otherwise the connecting parts of such an apparatus or mill shown in the accompanying drawings are illustrative 25 of parts of my said original application.

The subject matter of this invention is also partly described in and certain features of the invention herein described, but not herein claimed, are claimed in my following 30 applications, viz: said original application for patent filed June 15, 1911, Serial No. 633,343, Patent No. 1,243,050; application for patent filed October 10, 1916, Serial No. 124,921, Patent No. 1,243,051; application for 35 patent filed November 20, 1916, Serial No. 132,372, Patent No. 1,243,052; application for patent filed November 22, 1916, Serial No. 132,815, Patent No. 1,243,053; application for patent filed January 10, 1917, Serial No. 40 141,558, Patent No. 1,246,067; application for patent filed June 22, 1917, Serial No. 176,838; application for patent filed October 11, 1917, Serial No. 195,922; application for patent filed November 9, 1917, Serial 45 No. 201,036; application for patent filed November 9, 1917, Serial No. 201,155.

This invention relates to a novel and useful method or process and means for the manufacturing or the making of rolled car 50 wheels, disk-wheels, or other circular bodies from properly heated ingots, blooms, blanks or other work-pieces.

In my said original application, the car wheel or other circular body is centrally

pierced or penetrated or centered and is 55 rolled or formed by rolls operating against the opposite sides and against the peripheral face of the work-piece and is dished while the work-piece is rotated by said rolls.

Applicant is aware that heretofore it has 60 been proposed to roll car wheels on a forming-die shaped to conform to the center or hub part, the web part and the rim part at one entire side of the car wheel to be formed and also conform to the outer or 65 peripheral face of the car wheel, the car wheel being rolled on its other side only; that is, at one side of its web and at one side of the edge of its rim. During such rolling action, a work-piece of a given diameter 70 will be rolled to much larger diameter and to the form of a car wheel, such larger diameter being determined and governed by said forming-die. With such an arrangement, the metal in the work-piece is not 75 worked at its outer peripheral face and therefore will be extended instead of compressed; thus producing incipient cracks in the tread or outer peripheral face of the rim of the car wheel.

In this invention the car wheel or similar circular article is first formed by combined roll-forging and die-forging means into undished form and is then dished while the same revolves, or left undished, it being pierced or penetrated or centered and rolled at one side, thereby forcing metal of the work-piece against the forming-die, against or over a center or piercer passed axially through said forming- 85 die or formed integral with said die, and into the depressed portion or portions of said die, and also beyond and over the peripheral edge of said die, the actual forming portion of the preferred forming-die 90 reaching only to the inner peripheral face of the rim of the car wheel or other article at one side thereof when finished and being shaped to conform to the center or hub part and the web part and the inner peripheral 100 or inner circumferential face of the rim portion of the finished rolled or formed car wheel or other circular body at one side thereof; all other portions or surfaces of the car wheel or other body being rolled or 105 formed directly by rolls and, the car wheel or other circular body being dished while the same revolves or being left undished, all as

and in the manner hereinafter shown and described. During the entire rolling or operating process the metal at the peripheral face of the work-piece is worked by a roll or 5 rolls, whereby the metal in the whole rim portion is rolled or worked to uniform and maximum density, or practically so.

Another object of my invention is to provide for the manufacture of car wheels and 10 the like in an economical, commercial, expeditious and efficacious manner, whereby the whole car wheel may be completely rolled or formed and be dished or be not dished, from a properly heated ingot, bloom, blank 15 or other work-piece, including the piercing, or penetrating, or forming at the opposite sides of the work-piece of a rudimentary bore, or a part or parts thereof, in a simple and thoroughly practicable manner with the 20 same heat and before the finished rolled and dished or undished wheel, as the case may be, is removed from the apparatus or mill, while at the same time securing a uniform and maximum density and homogeneity in 25 the metal therein, which contributes materially to the strength and durability thereof. For instance, the metal, when being rolled or formed from a blank or other work-piece into a car-wheel or other circular object 30 according to my invention, is not expanded radially; especially is this avoided in the tread and flange or rim portion and therefore there is no possibility of the formation of incipient cracks in the tread and flange 35 portion or in the peripheral face of the rim. With my invention the metal in the work-piece is truly rolled or formed and increases in density with increased working, thus giving to the metal both its due maximum strength and maximum resistance to 40 wear. In other words, this invention of rolling or forming produces the same effect in the metal of the rim portion as if the web portion of the wheel were not in existence and the rim portion rolled or formed its 45 total width on its inner peripheral surface or surfaces, as is done on its outer peripheral surface consisting of the tread and flange.

A further object of my invention is to 50 provide method and means as hereinafter described by which a properly heated ingot, bloom, blank or other work-piece may be centered, or pierced, or penetrated and centered, or both centered and pierced or penetrated at one or both sides and also supported, and therefrom, with the same heat and in the same apparatus or mill, a car wheel or other circular article may be 55 completely rolled or formed. By such means and method as herein shown and described, the time required in so producing car wheels or other circular articles is much lessened and the cost of making such wheels or other articles is enormously reduced.

60 65 In carrying out this invention I employ

a continually and automatically acting clamping process or method and means to prevent the work-piece from becoming loose between its supporting means, such as or similar to the process for instance fully 70 described in my said original application; that is to say, for instance, the metal in a properly heated work-piece is very soft in comparison with the metal in its normal or cold condition and therefore has not the 75 required resistance, which is absolutely necessary for firmly supporting the work-piece, and on which account the work-piece will become loose between or on its supporting means during the operating process against 80 the work-piece if the work-piece would be centrally supported or held by means of screws or similar mechanism. To avoid this, I put the work-piece automatically into continually clamped condition between its 85 supporting means, by applying pressure centrally against the work-piece, which pressure acts continually and automatically against the work-piece from opposite sides. The work-piece or wheel, while centrally 90 supported by its supporting means, is therefore also automatically put into clamped condition, which prevents the hub or center portion of the work-piece from becoming loose on its supporting means and from being forced out of its true axial or central and desired lateral positions with respect to the rim portion of the work-piece or wheel during the rolling or operating processes, &c. Said constant clamping force or constant clamping pressure automatically and continually remains during said operating processes, and for moving the hub or center portion of the work-piece axially in either 95 direction while the same is so supported and so firmly clamped, all as hereinafter fully described and also described in my said original application.

Another object of my invention is the provision of a novel method and means for completely centering or piercing or penetrating and supporting properly heated ingots, blooms, blanks or other work-pieces and rolling or forming and dishing the work-piece to desired form while so supported; for rolling, forming or shaping a hub on a work-piece whereby the hub is formed smooth on all its surfaces to its desired form or shape without leaving a raised portion or fin which would have to be removed afterward by 110 turning or other costly means; for rolling or forming the inner peripheral face or faces of the marginal or rim portion of a work-piece or wheel sufficiently inclined outwardly toward the outer peripheral face 115 of the work-piece or wheel, as and for the purpose hereinafter described and also as described in my said original application; for rolling of the total peripheral face of the work-piece or wheel first to beaked form, 120 125 130

as and for the purpose hereinafter described and also described in my said original application, and then rolling the so beaked peripheral face to desired finished form 5 without leaving a raised portion or fin which would have to be removed afterward by turning or other costly means.

Another object of my invention is to provide a novel method and means for rolling 10 or forming and dishing car wheels or other circular objects, or for rolling or forming undished or dished car wheels or other circular undished or dished objects; for dishing, undishing or redishing car wheels or other 15 circular objects while rotating; for rolling metal from the rim portion onto the web portion during the rolling and dishing process; for centering a work-piece and sizing and compressing the hub portion thereof 20 while in properly heated condition; and, for decreasing the diameter of the bore in a car wheel or other circular work-piece by diametrically compressing the metal of the hub portion of the work-piece.

25 Further objects of my invention are to provide a novel method and means for rolling or forming a car wheel or other circular, or approximately circular, work-piece so as to cause metal in the same to flow in lateral 30 and radial lines, or substantially so, for the purpose of forming successively or alternately the web, the hub and the rim of said car wheel or other work-piece; for limiting the lateral flow of metal at the hub or at 35 the marginal or rim portion, or at both said hub and rim portions; for rolling the peripheral face or flanged tread of the rim portion of said car wheel or other work-piece to true circular form and thereby also uniformly 40 condensing the metal in said rim portion to maximum; for rerolling, reforming or reworking a car wheel or other similar object; and, for utilizing car wheels or reworking the same to form other circular objects 45 therefrom.

A still further object of my invention is to provide a method and an apparatus or mill wherein means or devices are systematically arranged, whereby car wheels, disk-wheels, 50 pipe flanges or other circular or similar bodies or articles may be rolled or formed and dished either with use of the forming-die and all the rolls, or for instance with use only of the forming-die, the herein 55 named edging and web rolling roll, the edging and die-supporting roll and the tread or face rolling roll; or, with use only of the forming-die, the herein named edging and web rolling roll, the edging and die-supporting roll, the tread or face rolling roll and 60 tread or face finishing roll; or, with use only of the forming-die, the herein named web finishing roll, the herein named die-supporting roll, and the tread or face finishing roll; 65 or, with use only of the forming-die, the

hersin named web finishing roll, the herein named die-supporting roll, the tread or face finishing roll, the herein named edging and web rolling roll and the edging and die-supporting roll; and, wherein the rolls and 70 their various devices or means for operating them, are so arranged for carrying out the rolling or forming with either the forming-die and all the rolls, or only with the forming-die and any of the combination of rolls 75 above mentioned. The various parts are so arranged that said apparatus or mill actually consists of two mills made in one, each of which may be operated and used separately or independently of the other mill, 80 which other mill will not, in such case be used. Said two mills are located one at each side of the axes or extended axes of the piercers or work-supporting centers and dishing device. One of said mills is herein named 85 the roughing mill or the roughing side of the apparatus or mill, although car wheels, disk-wheels, pipe flanges or other articles may be rolled or formed therewith to the finish, and consists of the forming-die, the herein named 90 edging and web rolling roll, the edging and die-supporting roll and tread or face roughing roll. The other of said two mills is herein named the finishing mill or finishing side of the apparatus or mill and consists of the 95 forming-die, the herein named web finishing roll, the die-supporting roll and tread or face finishing roll. The centering or the piercing and centering and the work-supporting and dishing device and also the raising, lowering and retaining device shown 100 and described in my said original application are all located at the center and between said two mills and may all be used with either of said two mills or with the whole 105 apparatus or mill, as the case may be.

In the manufacture of car wheels or other circular objects according to my invention, the cost of operation is greatly reduced. The production of car wheels and the like 110 is thereby greatly cheapened, the output increased, and the metal, for instance, in the tread and flange or the peripheral face and the whole rim portion of car wheels is rolled and is thereby uniformly condensed to its 115 maximum or substantially so, thereby giving the metal in said peripheral face and rim portion its due maximum and uniform strength and its due maximum and uniform resistance to wear, and thereby the said 120 peripheral face and rim portion of the car wheel is also rolled smooth on all its surfaces to the desired form or shape without leaving a raised circular portion or fin which would have to be removed afterward by turning or 125 other costly means.

It is, of course, understood that the various steps herein described may all be performed, in accordance with my invention, in the same apparatus or mill with one heat, or 130

each of said steps may be effected with a separate heat treatment of the work-piece and separate operation, as for instance described in my said original application. It will however, be apparent that any step or operation may be completed to partly roll or form the work-piece and later be operated upon in the performance of any other step or steps, as may be required, but it is to be understood that all the steps of my method herein described are necessary in the manufacture of a complete car wheel or other similar body to embody therein all the advantages of my invention.

15 Further objects of the invention will hereinafter appear.

20 My invention consists in the novel method or process herein described and more particularly pointed out in the claims; and it also consists in the novel means, in the arrangement thereof, in the novel features of construction and in the arrangement and combination of parts herein described and more particularly pointed out in the claims.

25 I prefer to carry out my invention with an apparatus or mill of the type or kind as for instance described and claimed in my aforesaid original application and in applications filed by me and having the hereinbefore mentioned serial numbers and filing dates, as will be made clear hereinafter.

In the accompanying drawings, in which I illustrate my invention together with devices or means I prefer to employ in carrying out my invention:

Figure 1 is a sectional plan view illustrating the main operating parts of one form of an apparatus or mill, such as I prefer to employ for rolling or forming car wheels or other circular bodies, and such as for instance shown and described in my aforesaid original application, with the exception for instance of said forming-die and of the modifications of one or both work-supporting heads and of rolls which also support said forming-die and of the modifications of details and of the modifications of operations, &c., all as hereinafter more fully shown and described. The work-piece is not shown in said Fig. 1, but the work-piece will be placed near or against said forming-die and between the piercers or work-supporting centers as hereinafter fully shown and described.

5 Fig. 2 is a side elevation of one of the oscillating frames; that is, the oscillating frame for the roll shaft having said edging and web rolling roll shown in Fig. 1, and shows the manner of supporting, guiding, positioning, shifting and driving said shaft.

Fig. 3 is a plan view of a portion of the said edging and web rolling roll shaft with its roll, a portion of its supporting means and the gage rods, of which in this figure three are shown, whereby the radial posi-

tions of said roll against the work-piece and the range of movement of said roll radially with respect to the work-piece are determined, as hereinafter described and also described in my said original application.

70 Fig. 4 is a cross-section taken on line 4—4, Fig. 3, looking in the direction of the arrows at said line.

75 Fig. 5 is a sectional plan view of a modified form of the main operating parts of the apparatus or mill shown in Fig. 1. The work-piece is not shown in Fig. 5, but the work-piece will be placed near or against said forming-die and between the piercers or work-supporting centers, as hereinafter 80 fully shown and described.

85 Figs. 6, 7 and 8 are sectional plan views of a portion of one form of the apparatus or mill showing my method and device for centering or for piercing or penetrating and centering, for rolling, and for dishing, for instance, flanged car wheels; therein an ingot, bloom, blank or other work-piece may also be centered or pierced or penetrated and centered and rolled and dished 90 with the use of the forming-die and with all the rolls of the apparatus or mill as herein shown and described, and the releasing of the work-piece or finished product, all as hereinafter fully described.

95 The parts shown in Figs. 9 to 16 inclusive are modifications of those shown in Figs. 6, 7 and 8, as hereinafter fully described.

Figs. 17 to 24 inclusive, for instance, illustrate somewhat modified forms of the apparatus or mill illustrated in the Figs. 1 to 100 16 inclusive, as hereinafter described.

Fig. 25 is a sectional side elevation, on enlarged scale, showing the adjacent ends of the supporting heads, the piercers or centers 105 supported thereby, the forming-die supported on one of said piercers or centers, and some of the rolls; therein is also shown a work-piece rolled or formed and dished to the finished rolled and dished form of the 110 dished car wheel shown at F².

Fig. 26 is a similar sectional side elevation, showing one of the supporting heads provided with roller-supports acting against or in contact with the marginal portion of 115 the forming-die; therein is shown a work-piece rolled or formed to the finished form of the undished car wheel shown at F².

Fig. 27 is a sectional end view of one of said roller-supports together with its 120 bracket.

Fig. 28 is a sectional view taken on line 28—28, Fig. 27, looking in direction of the arrows at said line.

125 Fig. 29 is a horizontal section through part of the supporting axle and the inner end of one of the supporting heads, as shown and described in my said original application.

Figs. 30 to 41 inclusive illustrate on en- 130

larged scales the device for longitudinally moving or operating one of the supporting axles together with its piercer or center independent of its supporting head, or for 5 moving said supporting head together with the supporting axle and its piercer or center, as hereinafter fully described.

Fig. 42 is a plan view of Fig. 43.

Fig. 43 is a sectional view through line 10 43-43, Fig. 42, showing the forming-die in diametral section and the parts shown are in proper position to receive a work-piece, as hereinafter fully described. In this figure the piercer or center is longitudinally 15 moved together with its supporting head, as indicated by the dotted line.

Figs. 44 and 45 are similar sectional views 20 as Fig. 43 and show different forms of the forming-die and rolls associated with the forming-die.

Fig. 46 is a sectional view showing the forming-die and the work-piece or finished product in diametral sections. In this figure is shown a rolled or formed and dished disk- 25 wheel or center such as used for instance in tired car wheels; otherwise this illustration is similar to the illustration in Fig. 18. Said disk-wheel or center is rolled or formed with the forming-die, one of the herein named 30 edging and web rolling rolls, one of the herein named edging and die-supporting rolls, and a single face roll as shown, and it is dished into the form shown, as and in the manner hereinafter described.

35 Fig. 47 is a sectional view similar to Fig. 46. In this figure is shown a rolled or formed and dished car wheel similar to Fig. 20. Said dished car wheel is rolled or formed with the forming-die, one of the 40 herein named edging and web rolling rolls, one of the herein named edging and die-supporting rolls, a face rolling roll, and a face finishing roll as shown, and it is dished into the form shown, as and in the manner hereinafter described.

Fig. 48 is a similar sectional view. The dished car wheel shown in this figure is rolled or formed with the forming-die, one of the herein named web finishing rolls, 50 one of the herein named die-supporting rolls, a face rolling roll, and a face finishing roll as shown and as hereinafter described.

Fig. 49 is a similar sectional view; in 55 this figure is shown a rolled or formed and dished car wheel similar to Fig. 24. Said dished car wheel is rolled or formed with the forming-die, one of the herein named edging and web rolling rolls formed wholly 60 cal as shown, one of the herein named edging and die-supporting rolls, one of the herein named web finishing rolls, one of the herein named die-supporting rolls, and a face finishing roll, all as shown; and it is 65 dished, as hereinafter described.

Fig. 50 is a similar sectional view as the one shown in Fig. 43 with the exception that in Fig. 50 the supporting axle with its piercer or supporting center is longitudinally moved or operated independent of its 70 supporting head.

Figs. 51 to 67 show sectional views illustrating various combinations and different forms of rolls, piercers or centers, and forming-dies. These figures illustrate, in accordance with my invention, certain piercing or centering or supporting steps and forming or rolling and forming steps for producing the dished car wheel shown for instance in the Fig. 54, 57, 61, 63 or 67, or 80 other figures, as hereinafter described.

Fig. 68 is a sectional view showing a portion of another form of the forming-die and the centering or supporting means. Therein is shown only the center portion of both 85 the work-piece and forming-die.

Fig. 69 is a sectional view showing the central portion of the work-piece provided with a large central opening and still another form of centering means in which the centering element at one side of the work-piece is integral with the forming-die. Therein is also shown only the central portion of the forming-die.

Fig. 70 is a sectional view showing the 95 central portion of the work-piece previously formed as shown and provided with central depressions or pockets into which the piercers or centers are to be penetrated or entered, one of said piercers or centers 100 being shown slidable within the forming-die. Therein is also shown only the central portion of the forming-die.

Fig. 71 is a sectional view showing the 105 central portion of the work-piece provided with an axial or approximately axial opening and showing different forms of centering elements at opposite sides of the work-piece, the centering element at one side being in the form of a piercer or center and the other being in the form of a forming-die which also serves in forming a hub portion onto the work-piece and which forming-die is keyed or otherwise securely fastened to the work-supporting axle. Therein 115 is also shown only the central portion of the forming-die.

Fig. 72 is a sectional view showing a 120 work-piece previously formed as shown and placed on the forming-die and, also showing the centering means. Therein is shown only the central portion of both the work-piece and forming-die.

Figs. 73, 74 and 75 show diametral sections of various additional forms of ingots, 125 bloom, blanks or other work-pieces.

Figs. 76, 77 and 78 show diametral sectional views of car wheels rolled or formed in accordance with my invention, the same being shown with the hub bored. In Fig. 13

76 said car wheel is shown dished. In Fig. 77 said car wheel has its web formed in undished position; that is, at right angles with the axis of the wheel, but the hub of 5 this wheel is not formed central to the web but is formed into the position required of a dished wheel, that is, the hub is in the same position as is the hub in Fig. 76. In Fig. 78 said car wheel is shown undished.

10 Figs. 79 to 82 illustrate, according to my invention, certain piercing and rolling or forming steps for producing the dished car wheel, for instance shown in Fig. 82, all as hereinafter described.

15 Fig. 83 is a sectional view showing side rolls substituted for the forming-die and its coacting rolls, whereby with the assistance of the rolls on the opposite side, the car wheel may be dished, or dished and rolled 20 after being rolled or formed to the form for instance shown in Fig. 81.

Fig. 84 is a sectional view showing a work-piece provided with an opening somewhat off-center and illustrating the method of 25 piercing or penetrating the work-piece centrally, regardless of the position of the opening therein.

Fig. 85 is a diametral section of the 30 completely rolled or formed and dished car wheel of Fig. 82 taken on line 85—85, Fig. 86, showing the inner peripheral surface of the rim at one side of the work-piece formed to a different angle than the inner peripheral surface at the other side thereof.

35 Fig. 86 is a fragmentary plan view of the completely finished car wheel of Fig. 82, rolled or formed in accordance with my invention herein described.

40 Fig. 87 is a diametral section of a car wheel completely rolled or formed and dished in accordance with my invention herein described and showing the inner peripheral face of the rim at one side of the car wheel formed to the same angle as the 45 inner peripheral face at the other side thereof.

Fig. 88 shows a sectional view similar to Fig. 43 or Fig. 50 with the exception that 50 the die-supporting portion of the side rolls and the forming-die in Fig. 88 are formed somewhat different.

55 Figs. 89 and 90 show the inclination or angle of the peripheral forming-edge or face of the forming-die somewhat different, the operating process or steps being similar to the ones shown in Figs. 79 to 82.

Figs. 91 to 94 inclusive, illustrate, according to my invention, certain rolling or forming steps in rolling or forming the finished 60 rolled undished car wheel shown in Fig. 94, all as hereinafter described.

Figs. 95 and 96 illustrate, according to my invention, certain rolling or forming steps in rolling or forming the dished disk-wheel or center with the forming-die and

70 piercers or centers formed as shown, and with all the rolls, of which each is formed as shown, and as hereinafter described.

Figs. 97 and 98 illustrate, for instance, certain steps according to my invention for 75 reworking or rerolling a car wheel, including the reworking of its hub portion.

Figs. 99 and 100 show, for instance, certain steps according to my invention for 80 rolling or forming disk-wheels, pipe flanges, 75 or similar articles from ingots, blooms, blanks or other work-pieces or for reworking car wheels or other circular objects into disk-wheels, pipe flanges or similar articles as hereinafter described.

Fig. 101 is a sectional view showing a different combination of rolls, combined with different forms of piercers or centers. Therein is shown the forming-die driven by gear teeth formed thereon meshing with the teeth 85 formed on the edging and die-supporting roll, which is positively driven from its shaft.

Fig. 102 is a transverse section taken on line 102, Fig. 101.

Fig. 103 is a sectional plan view of a 90 differently formed forming-die than the one shown in Fig. 101. In this figure, the forming-die is also shown driven by teeth similar to the teeth in Fig. 101.

Fig. 104 is a transverse section taken on 95 line 104, Fig. 103.

Fig. 105 is an enlarged sectional view showing in detail the supporting means for the forming-die and the rolls coacting therewith shown in Fig. 5.

Fig. 106 is a sectional elevation of the 100 same.

Fig. 107 is an end view with the piercer or center and forming-die removed and the supporting axle shown in section.

Figs. 108 and 109 show in detail the spindles for supporting the die-supporting rolls shown in Fig. 105.

Figs. 110 and 111 illustrate diagrammatically improper flow of metal resulting from 110 improper working of the metal in the rim portion of a car wheel or other circular object having a web, during the forming of said rim portion, all of which is avoided by my invention, as hereinafter described and 115 also described in my said original application.

Fig. 112 illustrates, for instance, the proper flow of metal during the forming of a tire having no web, such as used for some 120 tired car wheels, as hereinafter described and also described in my said original application.

Figs. 113 and 114 are diagrammatic illustrations showing the result of the rolling or 125 forming of the rim of a car wheel in accordance with my invention as hereinafter described, and also described in my said original application.

Figs. 115, 116 and 117 are similar dia- 130

grammatic illustrations showing the result of the rolling or forming of the rim of a car wheel or other circular body directly to finished form in accordance with my invention herein described. Fig. 116 shows the rim portion rolled with its flanged tread direct to finished form with the exception of rounding the outer corners of the flange and tread, and Fig. 115 shows said corners rounded with a separate finishing roll. Fig. 117 shows the rim portion having a straight peripheral face rolled direct to desired finished form.

Figs. 118 to 121 inclusive, show the flange and tread portions of car wheels and are diagrammatic views illustrating for instance a few shapes or ways of "beaking", as herein named and as hereinafter described and also described in my said original application.

It is, of course, to be understood that I do not intend to limit myself to the use of the particular parts herein shown nor the use of the remaining parts of the apparatus or mill shown and described in my said original application, as other means may hereafter be devised for carrying out my invention in a practicable manner.

Similar characters of reference indicate corresponding parts throughout the several views and, the parts of my said original application herein shown and not changed in this application have the same characters of reference as in my said original application.

B² designates part of the bed-plate which forms part of a suitable frame or foundation for carrying or supporting the various parts of my apparatus or mill as fully shown and described in my said original application.

E, E are the herein named work-supporting axles which may be made of different lengths and may be formed and constructed differently to suit the various purposes for which they are intended, as hereinafter described. These axles are rotatably supported in supporting heads M, M⁵⁰ and are arranged in alinement; one with its supporting head M being arranged at one side of the work-piece when the same is positioned in the apparatus or mill and the other with its supporting head M⁵⁰ being arranged at the other side of said work-piece or at one side of the forming-die as shown in the drawing. These axles in addition to serving to support the work-piece also serve other purposes as herein shown and described and they are longitudinally movable as hereinafter fully described.

One of said axles E, E, that is the one which is supported in the supporting head M, has one of the herein named piercers or supporting centers detachably secured to its inner or operating end, as shown. The other axle which is supported in the supporting head M⁵⁰ has one of the herein named piercers or supporting centers detachably

secured to its inner or operating end and which piercer or center is passed through the forming-die, as for instance shown, or is formed integral with the forming-die as for instance shown. Said axles are interchangeable for different lengths or differently formed axles, as may be required. Although so named these piercers or centers also serve other purposes as hereinafter described, and are longitudinally moved or operated as hereinafter described.

Said piercers or supporting centers for the axle in the supporting head M are interchangeable, either on said axle or with said axle, and may have many different forms or shapes as for instance: E¹ in Fig. 64 or 72; E² in Fig. 97; E³ in Fig. 68; E⁴ in Fig. 69; E⁵ in Fig. 71; E⁶ in Fig. 1, 5, 6, 7, 8, 12, 15, 17, 19, 21, 23, 25, 26, 29, 46, 47, 48, 49, 70, 79, 83, 84, 89, 95, 96, 99 or 100; E¹⁵ in Fig. 55, 58, 62, 102 or 103, &c. There is practically no limit to the forms or shapes that said piercers or supporting centers may have, as will appear from the matter hereinafter described.

Said piercers or supporting centers with the forming-die for the axle in the supporting head M⁵⁰ are interchangeable, either on said axle or with said axle, and may have many different forms or shapes, as for instance: E⁹ in Fig. 1, 5, 6, 7, 8, 12, 17, 19, 21, 23, 25, 30, 31, 40, 43, 45, 46, 47, 48, 49, 50, 64, 70, 79, 84, 88, 89, 95 or 105; E¹⁰ in Fig. 91; E¹¹ in Fig. 100; E¹² in Fig. 26; E¹⁴ in Fig. 51; or as for instance E¹⁶ in Fig. 55, 58, 62, 101 or 103, &c. There is practically no limit to the forms or shapes that said piercers or centers may have, as will appear from the matter hereinafter described.

Said piercer or supporting center for the axle in the supporting head M⁵⁰ has one of the herein named forming-dies, for instance W¹, W² or W³, &c., which dies may have many different forms or shapes, as for instance: W¹ in Fig. 1, 6, 7, 8, 12, 17, 19, 21, 23, 25, 26, 42, 43, 50, 70, 79, or 84; W² in Fig. 88; W³ in Fig. 97; W⁴ in Fig. 99; W⁵ in Fig. 100; W⁶ in Fig. 51; W⁷ in Fig. 89; W⁸ in Fig. 91; W⁹ in Fig. 95; W¹⁰ in Fig. 44; W¹¹ in Fig. 45; W¹² in Fig. 46, 47 or 64; W¹³ in Fig. 48 or 59; W¹⁴ in Fig. 55; W¹⁵ in Fig. 68; W¹⁶ in Fig. 69; W¹⁷ in Fig. 71; W¹⁸ in Fig. 72; W¹⁹ in Fig. 58; W²⁰ in Fig. 62; or as for instance W²¹ in Fig. 101, or as W²² in Fig. 103, each of which forming-dies W²¹ and W²² has a bevel gear formed at its one side meshing with a bevel gear driven from shaft J, as shown, and whereby said forming-die is positively driven or rotated; or as for instance W²³ in Fig. 5, 40 or 105, &c. Said forming-die is supported by said piercer or center in such manner that while it is rotated by rolls or the work-piece or by both rolls and the work-piece, during the operating process,

as hereinafter described, it also rotates said piercer or center together with the axle to which said piercer or center is secured, by means as for instance shown and described 5 with reference to Figs. 101 to 104 inclusive. Said forming-dies may also be supported and rotated as for instance hereinafter described. Each forming-die in preferred form is of a diameter which reaches only to 10 the inner peripheral face of the rim at one side of the finished car wheel or other finished circular object and is shaped to conform to the center or hub and the web part and the inner peripheral or inner circumferential face of the rim portion of the car 15 wheel or other circular body at one side thereof. Inside of the inner peripheral face of said rim the forming-die is shaped to conform with the shape or form which 20 the undished car wheel or other object is to have at said one side inside of said inner peripheral face of the rim portion, as shown.

All other portions or surfaces of the work-piece are rolled directly by rolls, as herein- 25 after more fully described. During the entire rolling or operating process, with the forming-die in said preferred form, the metal at the peripheral face of the work-piece is worked directly by a roll or rolls.

30 Said forming-dies are each formed to provide the work-piece at one side thereof with a hub portion, a web portion and an inner peripheral face of a marginal or rim portion, or they are formed as and for the 35 purpose hereinafter described.

F, F¹ and F² designate the work-piece from some of the various forms or shapes it may have when put into the apparatus or mill to some of the many various forms 40 or shapes which the finished article or product may have. For instance, F designates the ingot, bloom, blank or other work-piece in a few of the many various forms or shapes it may have when put into the 45 apparatus or mill, either solid, as for instance F in Figs. 64, 68 and 79, or it may be previously formed or pierced, as for instance F in Figs. 51, 55, 58, 62, 71, 72, 75 and 84; or it may have a central hole, 50 as for instance F in Fig. 69 or 74; or as F¹ in the Fig. 97; or previously formed into form or shape, as for instance F in Fig. 21, 23, 70, 73 or 74; or previously cast into any suitable form or shape, as for instance 55 F in the Fig. 21, 23, 73 or 74; or it may be a previously formed or rolled car wheel or other previously formed body to be re-worked or rerolled, as for instance the car wheel or work-piece shown at F¹ in Fig. 97, 60 which is shown reworked or rerolled to the form or shape shown at F² in Fig. 98. Such previously rolled or otherwise formed car wheel or other article to be rerolled or re-worked in my apparatus or mill may also 65 have any of the forms or shapes shown at

F² in Fig. 46, 76, 77, 78, 96, 98, 99 or 100, or as shown at F¹ in Fig. 59 or 95. There are a great many forms or shapes that the ingot, bloom, blank or other work-piece, or previously finished article may have when 70 put into the apparatus or mill, as will appear from the matter hereinafter more fully described; or, as for instance F², which represents the finished article or finished product from my apparatus or mill, 75 either dished or not dished.

J, J designate the roll shafts, one of which has at its inner or operating end one of the herein named edging and web rolling rolls, and the other has at its inner or 80 operating end one of the herein named edging and die-supporting rolls. Although so named, these rolls also serve other purposes as hereinafter described.

Said edging and web rolling rolls are 85 interchangeable and may have many different forms or shapes, as for instance J¹ in Fig. 1, 2, 5, 6, 7, 8, 12, 15, 16, 17, 19, 46, 47, 51, 79, 83, 89, 95 or 97; J² in Fig. 23 or 49; J³ in Fig. 91; J⁴ in Fig. 99 or 100; or 90 as for instance J⁵ in Fig. 55, 58, 62 or 64, &c. Said edging and web rolling roll may be either removably attached to its shaft in such a way that the whole roll may be driven by its shaft, or only part of the roll 95 may be driven by its shaft and the other part or parts be permitted to turn loose; or the whole roll may be permitted to turn loose on a journal formed on its shaft or on a journal removably fastened to its shaft, 100 all as fully described in my said original application. There is practically no limit to the form or shape that this roll may have, as will appear from the matter hereinafter described.

105 F, F¹ and F² designate the work-piece

interchangeable and may have many different forms or shapes, as for instance J⁶ in Fig. 1, 6, 7, 8, 12, 17, 19, 23, 43, 50, 79 or 89; J⁷ in Fig. 95 or 97; J⁸ in Fig. 44, 46, 47, 110 49, 51, 55 or 64; J⁹ in Fig. 45; J¹⁰ in Fig. 88; J¹¹ in Fig. 99 or 100; J¹² in Fig. 58; J¹³ in Fig. 62; or as for instance J¹⁴ in Fig. 101, which roll J¹⁴ has at its end, for instance, a bevel gear j¹⁵ driven by its shaft J and meshing with a bevel gear w⁸ formed with the forming-die W²¹ and therewith driving said die W²¹ as shown; or as for instance J¹⁵ in Fig. 103, which roll J¹⁵ has at its end, for instance, a bevel gear j¹⁶ driven by its shaft J and meshing with a bevel gear w¹¹ formed with the forming-die W²² and therewith driving said W²², as shown; or as for instance X⁴ in Fig. 105, &c., which roll X⁴ turns loose on a journal pin or spindle X⁵ 115 as shown. Said edging and die-supporting roll for instance, J⁵, J⁶, J⁷, J⁸, J⁹, J¹⁰ or J¹¹ may be either removably attached to its shaft in such a way that the whole roll 120 may be driven by its shaft, or only part 125 as shown. Said edging and die-supporting roll for instance, J⁵, J⁶, J⁷, J⁸, J⁹, J¹⁰ or J¹¹ may be either removably attached to its shaft in such a way that the whole roll 130

of the roll may be driven by its shaft and the other part or parts be permitted to turn loose; or the whole roll may be permitted to turn loose on a journal or journals formed on its shaft or a journal or journals removably fastened to its shaft, all as hereinafter described. There is practically no limit to the form or shape that this roll may have, as will appear from the matter hereinafter described.

10 G, G designate the roll shafts, one of which has at its inner or operating end one of the herein named web finishing rolls, and the other has at its inner or operating end one 15 of the herein named die-supporting rolls. Although so named, these rolls also serve other purposes is hereinafter described.

Said web finishing rolls may have many 20 different forms or shapes, as for instance G¹ in Fig. 1, 5, 6, 7, 8, 12, 15, 16, 21, 23, 49, 51, 55, 62, 64, 79, 83, 89, 95 or 97; G⁵ in Fig. 25 99 or 100; G¹ in Fig. 91; or as for instance G⁵⁵ in Fig. 48 or 58, &c. Said web finishing rolls are interchangeable, as described 30 in my said original application. There is practically no limit to the shape that this roll may have, as will appear from the matter hereinafter described.

Said die-supporting rolls are interchangeable 35 and may have many different forms or shapes, as for instance G¹⁴ in Fig. 1, 6, 7, 8, 12, 21, 23, 43, 44, 49, 50, 51, 55, 64, 79, 89, 91, 95 or 97; G⁴⁵ in Fig. 45; G⁶¹ in Fig. 48; G⁶⁷ in Fig. 99 or 100; G¹⁰⁹ in Fig. 58; G¹¹⁰ in Fig. 62; G¹¹¹ in Fig. 101; G¹¹² in Fig. 103; G¹¹³ in Fig. 88; or as for instance X³ in Fig. 5 or 105, &c., which roll X³ turns loose on a journal pin or spindle X⁵, as shown. Said die-supporting roll for instance, G¹⁴, G⁴⁵, G⁶¹, G⁶⁷, G¹⁰⁹ or G¹¹³ may 40 be either removably attached to its shaft in such a way that the whole roll may be driven by its shaft, or only part of the roll may be driven by its shaft and the other 45 part or parts may be permitted to turn loose; or the whole roll may be permitted to turn loose on a journal or journals formed on its shaft or on a journal or journals removably fastened to its shaft. There is practically 50 no limit to the form or shape that this roll may have, as will appear from the matter hereinafter described.

K designates the herein named tread or face rolling roll which is adapted to act 55 against the peripheral face of the work-piece to roll said face to a beaked or rudimentary form, or to partly finished or to completely finished form and which roll during the rolling process is moved toward, 60 against or away from the peripheral face of the work-piece. The said movements of said roll are limited or controlled by adjustable stops provided in the mechanism for causing said movements, as hereinafter described, and by means of said stops the

radial distance or distances of said roll from the axis of the supported work-piece may be adjusted or controlled so as to suit any requirement and whereby said roll may be stopped and retained at any desired radial 70 distance from the axis of the supported work-piece. Said tread or face rolling roll is also supported so as to permit lateral movement of the same. The peripheral face of said roll may have also various different 75 shapes as for instance described in my said original application and as hereinafter more particularly set forth, and said face roll may also serve other purposes such as hereinafter fully described; there being practically no limit to the shapes which the peripheral portion of said tread or face roll may have, or to the purpose for which said face roll may be used.

H designates the herein named tread or 80 face finishing roll which is adapted to act against the peripheral face of the work-piece. This roll, during the rolling process, is moved toward, against or away from the peripheral face of the work-piece and the 85 movements of said roll are limited or controlled by adjustable stops provided in the mechanism for causing said movements, as hereinafter described, whereby the radial distance or distances of said roll from the 90 axis of the supported work-piece may be governed to suit the exact diameter of the car wheel when finished. After the car wheel has been rolled to its finished diameter, said roll acts as a rolling stop against 95 the peripheral face of the work-piece, car wheel or other article, and maintains said finished diameter during any further operations against said work-piece, wheel or other article. The peripheral face of said roll 100 may have also many different shapes, as for instance described more fully in my said original application, and as hereinafter more particularly set forth, and said face roll may also serve other purposes such as hereinafter 105 fully described; there being practically no limit to the shapes which the peripheral portion of said tread or face finishing roll may have, or to the purpose for which said face roll may be used.

Said face rolls H and K may also be 110 moved toward, against or away from the peripheral face of the supported work-piece, either together or independently of each other, as and in the manner hereinafter described and also as described in my said original application.

In rolling or forming for instance car 115 wheels or other circular articles having each a hub, a web and a marginal or rim portion, the lateral thickness or width of said face roll K, in most cases, is the same as is the lateral thickness or width which the outer or rim portion of the car wheel or other article is to have when finished, as is shown 120 125 130

for instance at K in the Figs. 6, 7, 17, 19, 46, 47, 52, 54, 66, 67, 81, 82, 83, 93, 94, 96 and 98. As shown in said figures, the opposite side faces of said face roll K are therefore adapted to act for gaging the lateral thickness or width which the marginal or rim portion of the car wheel or other circular article is to have when finished. In some cases said face roll K may be formed and be used as a face finishing roll, as for instance shown at K in Fig. 48, and in other cases said face roll may not be operating against the peripheral face of the work-piece, but may serve other purposes, as for instance shown at K in Figs. 58 to 61. Said face finishing roll H, in some cases, may have a lateral thickness or width which is the same as is the lateral thickness or width which the outer or rim portion of the car wheel or other circular article is to have when finished, as shown for instance at H in Fig. 48, in which case the opposite side faces of said face roll H serve to act for gaging the lateral thickness or width which the marginal or rim portion of the car wheel or other circular article is to have when finished; and in other cases said face roll H may not be operating against the peripheral face of the work-piece, but may serve other purposes, as for instance shown by the face roll H in Figs. 58 to 61.

Positioning, or raising, lowering and retaining device.

I prefer to employ a positioning, or raising, lowering and retaining device, such as for instance shown and described in my said original application, for taking the finished article or product out of the apparatus or mill, for putting the properly heated ingot, bloom, blank or other work-piece into the apparatus or mill and retaining the same in a position wherein its outer portion or periphery is central or coaxial, or approximately so, with the piercers or work-supporting centers and also central with said forming-die arranged on one of said piercers or centers to permit of its being centered or pierced or penetrated and centered in the center, or approximately in the center, of its outer portion or periphery with said piercers or centers and, when said work-piece is so pierced or penetrated or centered, it will also be central with said forming-die, and for lowering the supporting member of said device away from said work-piece, either after said work-piece is so centered or pierced or penetrated and centered or during said centering or piercing or penetrating process, and for retaining the supporting member of said device in said lowered position away from said work-piece until said work-piece or said finished article or product is to be taken out of the apparatus or mill, as and in the manner shown and described in my said original application.

With reference, for instance, to Figs. 1, 2, 3 and 4 illustrating the main operating parts of one form of my said apparatus or mill; the work-piece is not shown in said figures but will be placed between the piercers or centers, for instance E^a and E^b. Fig. 2 is a side elevation of one of the oscillating frames for one of the shafts J, J, that is, the oscillating frame for the shaft J having the roll J¹ shown in Fig. 1. In Fig. 3 is shown in plan view the end portion of one shaft J having for instance the roll J¹ and also the journal and guide piece J⁸ shown in Fig. 1, but in Fig. 3 are shown three gage rods J⁹, J¹⁰, J¹¹. Fig. 4 is a sectional end view through line 4—4, Fig. 3, looking in direction of the arrows. In said figures, M, M¹⁰ are the herein said work-supporting heads; although so named, they also serve other purposes, as will be observed from matters hereinafter described. One of the herein named work-supporting heads M, M¹⁰, that is the herein named work-supporting head M with its axle E and piercer or center, for instance, E^a is moved by the pressure in its pressure cylinder N operatively connected therewith, as for instance illustrated in Figs. 6, 7 and 8, forward and backward or in the same direction with the other piercer or center, for instance E^b, as the case may require, and its maximum back-movement is indicated by the dotted lines for said head M, axle E and piercer or center E^a (see Fig. 1). The distance of the maximum back-movement of the other herein named work-supporting head M¹⁰ with its axle E, is the same as for said head M, but such back-movement is in the opposite direction. The movements of head M¹⁰, axle E, piercer or center, for instance E^b, and forming-die, for instance W¹ (see Fig. 1), take place as and in the manner and for the purpose hereinafter described. The shafts J, J are each located and operated as illustrated in Fig. 1. One of said shafts J, J has at its inner or operating end one of the said herein named edging and web rolling rolls, for instance J¹, which roll may be moved inward laterally from the position shown in solid lines to the position shown by the dotted lines for J¹, in which latter position it is in contact with the face roll K as shown and it may also be moved laterally in the opposite direction to the position shown by the other dotted lines for J¹; said two positions of said roll J¹ shown in dotted lines indicating approximately the extreme lateral range of movement of said roll J¹, and when operating against work-pieces to be rolled or formed into different articles, said roll J¹ may have its axis either parallel or inclined to the side of the supported work-piece or to a plane at right angles to the axis of the supported work-piece, all as practice may determine and depending also

on the thickness and shape of the article to be rolled or formed from the work-piece. The other of said shafts J, J has at its inner or operating end one of said herein 5 named edging and die-supporting rolls, for instance J⁵⁹; which, in said Fig. 1, is shown with its die-supporting portion in contact with the forming-die, for instance W¹, and with its edging roll part in contact with the 10 face roll K as for instance shown. During the operating process said face roll K is continually in contact with or is operating upon the peripheral face of the work-piece and as the work-piece increases in diameter, said 15 face roll will be moved in the direction away from the axis of said piercers or centers, for instance E⁶, E⁹, and the edging roll part of said roll J⁵⁹ will roll or operate against or in contact with the edge or 20 side of the marginal or rim portion of the work-piece, as and in the manner herein-after fully described. The forming-die, for instance W¹ shown in Fig. 1, is provided 25 at one side thereof with a circular track or groove and the die-supporting portion of said roll J⁵⁹ is correspondingly shaped to fit said track or groove and support said forming-die during the operating process. The piercer or center, for instance E⁹, at 30 the end of the work-supporting axle E in said supporting head M⁵⁰ is passed axially through said forming-die W¹, as shown, and serves also to centrally support said forming-die and it is adapted to be moved 35 longitudinally with its work-supporting axle E, independent of said forming-die, as herein-after more fully described. In said Fig. 1, the other piercer or work-supporting center E⁶ is shown located with its axle E 40 and head M at one side of said forming-die W¹, but during the operating process against a work-piece it is located at one side of the blank or work-piece and preferably revolves with the work-piece and forming-die. With reference to Fig. 1; before a 45 work-piece is placed into the apparatus or mill, said forming-die W¹, die-supporting roll for instance G¹⁴, edging and die-supporting roll for instance J⁵⁹, and the piercer or center, for instance E⁹, with its axle E 50 and supporting head M⁵⁰ are moved into the proper position, as for instance shown, and they are retained in such position during the operating process until the work-piece or wheel is to be dished or rolled and dished. When the work-piece or wheel is 55 ready for dishing, either said piercer or center E⁹ with its axle E and supporting head M⁵⁰, or said piercer or center E⁶ with its axle E, will be moved or forced axially by 60 their power or pressure means operatively connected therewith, together with the hub or central portion of the work-piece or wheel and with said other piercer or center E⁶, so 65 as to move or force the center or hub portion

of the work-piece or wheel into its proper position of the dished work-piece or wheel, as and in the manner hereinafter fully described. During this dishing operation, the work-piece or wheel remains automatically 70 axially clamped firmly between said piercers or centers E⁶, E⁹, as and for the purpose hereinafter fully described and also shown and described in my said original application, and during said dishing operation the 75 said forming-die, together with the marginal or rim portion of the work-piece or wheel is laterally supported and retained by said rolls for instance J¹, J⁵⁹ and G¹, G¹⁴. During the piercing or penetrating or centering process, with reference to Fig. 1, the piercer or center, for instance E⁹, is moved longitudinally toward the other while said other piercer or center E⁶ and the forming-die supported thereby are retained in fixed 80 85 rotatable positions, or it may be otherwise moved as for instance hereinafter described with reference to Fig. 43.

Oscillating frames for the herein-named edging and web rolling rolls, and edging and die-supporting rolls.

In Fig. 1 are shown the two oscillating frames J¹⁵, J¹⁵ for said roll shafts J, J, each shown in horizontal sectional plan 95 through the axis of its roll shaft J; said roll shafts and parts connected therewith being shown in plan. In Fig. 2 the oscillating frame for the shaft J having the roll J¹ shown in Fig. 1, is shown in side elevation 100 and illustrates the shifting and driving arrangements for said roll J¹. The driving mechanism for driving said roll is connected to the shaft J¹⁸.

Each of said oscillating frames J¹⁵, J¹⁵ 105 is oscillated or swung forward and backward laterally on its lower trunnion J¹⁸⁸ and its upper trunnion J¹¹ by the power or pressure in its co-operating power or pressure cylinder, the piston of which is operatively connected to the journal pin J¹⁰⁴ 110 located in the bearing and guide piece J⁶, one cylinder and piston being provided for each roll for giving the same its lateral movements, as and in the manner for instance fully shown and described in my said original application. The lower frame part of the oscillating frame J¹⁵ is formed or provided with the trunnion part J¹⁸⁸ as shown. Said lower trunnion J¹⁸⁸ with its 115 inner sides forms a bearing or bearings for the vertical shaft J¹⁸. The housings J¹⁰ and J¹¹ of each of said oscillating frames are adjustably fastened with their lower ends to the lower frame part of their oscillating frame J¹⁵, and with their upper ends they are adjustably fastened to the upper part J¹⁴ 120 of said oscillating frame. Each of said trunnions J¹¹, J¹¹ of said oscillating frames is fitted and fastened to the upper part J¹⁴ 125 130

of its oscillating frame, as shown, and its axis is in line with the axis or extended axis of said vertical shaft J^{18} .

Each of said shafts J , J is provided with 5 feathers between said housings J^{10} and J^{11} , and a bevel gear J^{22} is slidably fastened to each shaft by means of said feathers. Each bevel gear is formed at its inner end with a long hub, as shown, which has a sliding fit 10 over its shaft J and over said feathers. By means of said feathers said shaft is driven or rotated by said bevel gear J^{22} . Between the inner sides of said housings J^{10} and J^{11} and the ends of said bevel gear J^{22} are 15 located ball thrust bearings whereby said bevel gear is kept in its proper position end-wise between said housings J^{10} and J^{11} and in proper mesh with a bevel gear J^{23} secured to its shaft J^{18} , as fully described in my said 20 original application. To each of the upper parts J^{14} , J^{14} of the oscillating frames, one being provided for each oscillating frame, are fitted and bolted the supporting brackets J^{28} , J^{28} and J^{29} , J^{29} for its shifting cylinder 25 J^{11} , as shown. Each of said shifting cylinders J^{11} , J^{11} , of which one is provided for each roll, is firmly but longitudinally and adjustably held by said supporting brackets and supported thereby.

30 Each of said shafts J , J is provided with one of said shifting cylinders J^{11} , J^{11} as shown in the Fig. 2, wherein is shown the shaft with its said roll J^1 and the piston-rod J^{19} of the shifting cylinder J^{11} , which rod, 35 by means of the double lever J^{97} , J^{97} , shifts or moves said roll shaft J with its said roll J^1 longitudinally alternately forward and backward to the positions for instance indicated for said roll J^1 by the dotted lines 40 thereof in Fig. 2. Each cylinder J^{11} has a piston with a piston-rod J^{19} and a piston-rod J^{80} passing through the cylinder heads J^{81} , J^{81} at both ends of the cylinder J^{11} . The piston-rod J^{80} at its outer end has firmly 45 fastened thereto the collar J^{124} and from there it is provided with a long thread J^{84} , over which is fitted a threaded adjustable nut J^{83} which is made in halves and when adjusted is firmly held together and to the 50 piston-rod J^{80} . This nut J^{83} can be adjusted from one end to the other end of said thread J^{84} , and with the end of the extension J^{102} of the packing box gland forms a stop for the piston stroke at this end of the cylinder. 55 By adjusting said nut J^{83} forward or backward, such as the case may require, the forward stroke of the piston is regulated and thereby the desired limit of the shifting movement of the said edging and web rolling 60 roll away from the center part and toward the rim part or periphery of the work-piece, wheel or other article is regulated or adjusted. To the outer end of the piston-rod J^{19} , the cross-head J^{88} is fastened with 65 a transverse key, or other suitable means,

and from there said piston-rod is provided with a long thread J^{87} over which is fitted the threaded adjustable nut J^{86} which is made in halves and when adjusted is firmly held together and to the piston-rod. This 70 nut J^{86} can be adjusted from one end to the other of said thread J^{87} , and with the end of the extension J^{85} of the packing box gland forms a stop for the piston stroke at this end of the cylinder. By adjusting said nut 75 J^{86} forward or backward, such as the case may require, the return stroke of the piston is regulated and thereby the desired limit of the shifting movement of the said edging and web rolling roll toward the center or 80 hub part of the work-piece, wheel or other article is regulated or adjusted. Said cross-head J^{88} , at both its outer sides is formed or provided with trunnions J^{91} . Links J^{90} are connected with one of their ends to said 85 trunnions J^{91} , and with their other ends to the journal pin J^{92} as shown, said links being located at the upper ends of said double lever J^{97} , J^{97} and connecting the upper ends of said double lever J^{97} , J^{97} with the cross-head J^{88} as shown. Lugs J^{90} are formed with the lower frame part of said oscillating frame J^{15} at one end thereof, as shown, and are provided with bearings for the journal pin J^{96} at one end of the link J^{95} . At its 95 other end, said link J^{95} is provided with a bearing for its other journal pin J^{94} . At each of the outer sides of said link J^{95} , the end parts of said journal pin J^{94} are fitted or fastened to the lower ends of said double 100 lever J^{97} , J^{97} , as shown; said double lever consisting of the like parts or levers J^{97} , J^{97} , as shown in the Figs. 1 and 2. Each roll shaft J at its outer end is provided with a thread over which is fitted the threaded 105 adjustable nut J^{102} which is made in halves and when adjusted is firmly held together and to the shaft J . Fitted to said shaft J between said nut J^{102} and a shoulder provided on the shaft, are the cross-head J^{88} and 110 thrust bearings located at each end of said cross-head J^{88} , as fully described in my said original application. Said cross-head J^{88} is provided at two of its opposite sides with the journals or trunnions J^{98} , J^{98} , whereby 115 said cross-head J^{88} is connected with the double lever J^{97} , J^{97} , as shown. Said cross-head does not revolve with shaft J and any end play or wear is taken out or adjusted by said nut J^{102} . Each roll shaft J , is as 120 before said, supported in the bearing of said guide piece J^8 and in the bearings of said housings J^{10} and J^{11} , and is shifted or moved longitudinally with said double lever J^{97} , J^{97} by the pressure in its said shifting cylinder J^{11} in the bearings of said parts J^8 , J^{10} and J^{11} and in said bevel gear J^{22} , forward and backward, such as the case may 125 require; said movements being effected by the pressure in said shifting cylinder J^{11} . 130

Each of said guide pieces J^s , one for each roll, see Figs. 1 and 2, is formed at its upper side with a lug to which is lengthwise adjustably attached the gage rod J^o , as shown, or two or more such gage rods may each be so adjustably attached to such lug or lugs, as shown for instance in Figs. 3 and 4, in which figures for instance three such gage rods are shown. Said gage rod J^o is formed at one end with a long thread which is provided with the nuts as shown, and its other pointed end is bent down, as shown. Each of said shafts J , J is provided with a circumferential mark or shoulder J^{152} as shown. In Fig. 2, the roll J^1 is shown in a position corresponding with the adjustable nut J^{83} while against the end J^{82} of the extension of the packing box at the one end of cylinder J^{17} . The dotted lines for the roll J^1 show said roll when moved into the position corresponding with that of the adjustable nut J^{86} when against the end J^{85} of the extension of the packing box at the other or lever end of cylinder J^{17} , as is shown by the dotted lines for said nut J^{86} , and the corresponding position of said double lever J^{97} , J^{97} is also shown by the dotted lines. When the gage rod J^o is adjusted, for instance, to its commencement position shown in Fig. 2, then in such case, the roll J^1 is shifted until said mark or shoulder J^{152} on said shaft J has reached the point of said gage J^o , as illustrated by the dotted line J^{152} , and in said position, the roll J^1 will be, for instance, approximately in the position indicated by the dotted lines for part of said roll J^1 , in which position the operation of the said roll J^1 against the work-piece may commence. Said gage rod or rods J^o can also be adjusted to any desired position or positions between said shifting limits to indicate a predetermined point or points from the center of the supported work-piece at which said roll may be retained against the work-piece or be stopped, as and in the manner more fully described in my said original application. In case it should be so desired that each of such positions of said roll or rolls, that is the position for starting and for stopping the shifting operation of said roll or rolls, should each be indicated; then in such case, another adjustable gage rod or rods similar to J^o will be attached next to said rod J^o to each of said guide pieces J^s , in a similar manner to rod J^o as for instance shown in said Figs. 3 and 4; and thereby, two or more gage rods, each similar to rod J^o , will be provided for said edging and web rolling roll J^1 and also for said edging and die-supporting roll J^{59} , if such be desired. The nuts on said gage rods J^o , J^o , &c., can be adjusted to the ends of the thread forward or backward, such as the case may require, whereby the points of said gage rods J^o , J^o ,

&c., can be adjusted to any desired position or positions of said rolls between their shifting limits.

Said edging and web rolling roll, for instance J^1 , and said edging and die-supporting roll, for instance J^{22} , may be shifted or moved longitudinally independently of each other; for instance, in such a way that said edging and die-supporting roll J^{22} is retained in contact with the forming-die, for instance W^1 , as shown, or in any other position between its shifting limits, as for instance may be required for other formed forming-dies herein illustrated; or, said rolls G^{14} , J^{22} with their shafts J , G may be substituted by rolls that do not move longitudinally, as for instance the rolls X^3 and X^4 in Figs. 5 and 105 hereinafter described, and said edging and web rolling roll, for instance J^1 , while operating on the work-piece, may be shifted forward and backward, such as the case may require, as for instance illustrated in Figs. 51, 52 and 53. In Fig. 51, the edging and die-supporting roll for instance J^{22} is retained in contact with the forming-die for instance W^1 , as shown, and the work-piece during the rolling process is pressed against said forming-die W^1 , which is supported by the edging and die-supporting roll J^{22} with practically the same pressure with which the edging and web rolling roll, for instance J^1 , may be pressed laterally against the work-piece, as shown for instance in Figs. 52 and 53. During the rolling process, the said roll J^1 is also shifted or moved longitudinally by the pressure in its cylinder J'' , as before described, and with its said web reducing part j^{22} operates on the web, hub and inner rim parts, and with its said edging roll part j^{22} operates upon the portion of the work-piece between said web reducing part j^{22} of said roll J^1 and the periphery of the work-piece at one side thereof. During the time the roll J^1 is shifted by the pressure in its coöperating pressure cylinder J'' from the position shown in dotted lines adjacent the hub portion, in Fig. 53, to the position shown in solid lines adjacent the rim portion of the work-piece, the edging roll part j^{22} of the edging and die-supporting roll, for instance J^{22} , is operating against the edge or side of the rim portion, and thus forms the web portion of the work-piece. During said web rolling or forming process, said roll J^1 has been shifted or moved longitudinally by the pressure in its coöperating pressure cylinder J'' and has been moved laterally by the pressure in its other coöperating pressure cylinder (the piston of which cylinder is operatively connected to the journal pin J^{104} located in said guide piece J^8 ; see Fig. 1). After such operation the dishing and finishing of the finished wheel F^2 shown in said Fig. 54 will

commence and be done as and in the manner hereinafter described and also described in my said original application.

Said edging and web rolling roll for instance J^{69} in Fig. 55, 58, 62, 64 or 66, is formed as shown, that is, each consists of the edging roll portion j^{29} , the web rolling or web reducing portion j^{28} and the hub end-face rolling portion j^{43} . With the roll J^{69} 10 in the position shown in Fig. 66 by the dotted lines adjacent the hub portion of the work-piece, said roll J^{69} with its said hub rolling portion j^{28} has rolled or formed the hub to its desired finished length indicated 15 by x^{12} and with its edging roll portion j^{29} it has rolled or formed the rim to its desired finished lateral width indicated by x^{10} , and during the longitudinal or approximately longitudinal movements of said roll J^{69} between the hub and rim portions the web 20 rolling portion j^{28} of said roll J^{69} has rolled or formed the web portion to its desired thickness indicated by x^{11} ; that is to say, when the edging roll portions j^{29} , j^{28} of the 25 rolls J^{69} , J^{61} are against or in contact with the opposite sides of the face roll K as shown, said hub rolling portion j^{43} has rolled or formed the hub to its desired finished length indicated by x^{12} and the web rolling portion 30 j^{28} has rolled or formed the web portion to its desired thickness indicated by x^{11} . From this it will be observed that with said edging roll portion j^{29} of said roll J^{69} as a basis, the diameters of said other portions j^{28} 35 and j^{43} are made to suit the length of the hub and the thickness of the web.

The edging and web rolling roll, for instance J^1 , in Figs. 79, 80 and 81 is formed similar to the edging and web rolling roll 40 J^{69} , last above referred to, with the exception that it has the hub end-face rolling portion j^{43} omitted. The web rolling or web reducing portion j^{28} is, however, similarly related to the edging roll portion j^{29} and 45 with said edging roll portion rolling in contact with the face roll K , the extent to which the thickness of the web is reduced is governed as described with reference to Fig. 55, 58, 62, 64 or 66.

50 *Oscillating frames for the herein-named web finishing rolls and die-supporting rolls.*

In Fig. 1 are also shown, in plan view with their upper parts removed, the two 55 swinging or oscillating frames on which are mounted in bearings G^{10} and G^{12} the roll shafts G , G . One of said shafts G , G has at one of its ends one of the herein named web finishing rolls, for instance G^1 , 60 and the other shaft G has at one of its ends one of the herein named die-supporting rolls, for instance G^{14} . Said shafts G , G consist each of the two sections G and G^1 65 and have for instance their rolls G^1 , G^{14} and their outer ends, adjacent or near the osci- 70

lating or free ends of said oscillating frames. Each of said shafts G , G is provided at its other or outer end with the coupling part G^{20} which is connected to a driving mechanism for said roll, such driving mechanism is not shown herein but is shown and described in my said original application. Said shaft section G is interchangeable with other similar shaft sections and is removably fitted into the socket portion G^9 of the shaft section G^8 . Said roll G^1 with its said shaft sections is longitudinally adjustable or movable in said bearings G^{10} and G^{12} , the distances indicated, for instance, by the dotted portion of the 75 lateral apex of said roll G^1 for said longitudinal movements, and during the operating process it is also laterally movable from the position of said roll G^1 shown in solid lines to its position next thereto shown in dotted lines, in which latter position it is 80 in contact with the face finishing roll H , as shown. Said roll G^1 may also be moved laterally from its said position shown in solid lines to its extreme position shown in dotted lines and indicated by its path shown 85 by the curved dotted line x , as and for the purpose described in my said original application. Each of said oscillating frames 90 swing or oscillate on a bearing or bearings provided in its hub shaped end for instance G^{17} and, when for instance said web finishing roll G^1 is moved or oscillated toward or against or away from the work-piece, it travels therefore, in a circular path which 95 has its center on the axis of the journal or pivot G^{20} , as shown in Fig. 1; that is, the circular path described by each of said rolls for instance G^1 , G^{14} , is concentric with the 100 axis of said bearing or bearings provided in said hub-shaped end G^{17} . Thereby is also produced the proper direction of pressure against the work-piece; this being one of the main purposes for locating the axis of said journal or pivot G^{20} a proper suitable distance away from the axis or extended axis of its roll shaft G , as for instance 105 shown and all as and for the purpose more fully shown and described in my said original application. 110

115 *Tread or face rolls H and K .*

With reference to Fig. 1; the face finishing roll H with its supporting or slide head H^3 is located between said shafts G , G and 120 their rolls, for instance G^1 , G^{14} , and is moved in guide or slide bearings at right angles with the axis of the work-piece, as shown, toward and against or away from the work-piece, such as the case may require, by means of pressure in the cylinder H^{27} , or by any other suitable means. Said cylinder H^{27} is bolted to the bed plate as shown and described in my said original application. The said pressure cylinder H^{27} 125 130

has a piston with a front piston-rod H^{20} which projects from the front end of the cylinder and a rear piston-rod which passes through the cylinder heads at the rear end 5 of said cylinder. The front piston-rod H^{20} is firmly attached at its outer end to said head H^s and the rear piston-rod is firmly attached near its end H^{26} to the cross-head H^{40} . From the cross-head H^{40} , the piston-rod is provided with a long thread H^{23} over 10 which is fitted a threaded adjustable nut H^{24} made in halves and firmly held together and to the piston-rod by means of screws. This nut H^{24} can be adjusted from one end 15 to the other end of said thread H^{23} and with the end of the extension H^{22} of the packing box gland forms a stop for the forward stroke of the piston in said cylinder H^{27} . By adjusting said nut H^{24} forward or 20 backward, as the case may require, the forward stroke of the piston in cylinder H^{27} is regulated and thereby the limit of the forward movement of the tread or face finishing roll H is adjusted. At a suitable 25 distance from the end H^{26} of said rear piston-rod is located an adjusting screw H^{34} which is formed at its end with the enlargement H^{35} forming a stop to limit the movement of the finishing roll H away from the 30 work-piece, and near its outer end said screw H^{34} is provided with a lock nut. Said screw H^{34} is firmly supported by the cross-piece H^{17} which is firmly connected with the cylinder H^s by means of upper and 35 lower distance rods, as shown and described in my said original application. The end H^{26} of said screw H^{34} forms with said end H^{24} of said rear piston-rod a stop for the pull-back stroke of the piston in cylinder 40 H^{27} , and by adjusting said screw H^{34} forward or backward, as the case may require, the pull-back stroke of the piston in cylinder H^{27} is regulated and thereby the limit of the return or pull-back movement of the 45 tread or face finishing roll H is adjusted.

Tread or face rolls H and K , movements, and pressure equalizing device, etc.

The said cross-head H^{40} is formed at each 50 of its lower and upper sides with a trunnion H^{41} , as and for the purpose fully shown and described in my said original application. A cross-head similar to the cross-head H^{40} is firmly attached to the rear end of the 55 piston-rod of the piston in the pressure cylinder K^{27} for the herein named tread or face rolling roll K , as and for the purpose fully described in my said original application.

With further reference to Fig. 1; the 60 herein named tread or face rolling roll K with its supporting or slide head K^{12} , is located between said shafts J , J and between the said edging and web rolling roll, for instance J^1 , and the said edging and die- 65 supporting roll, for instance J^{10} , and is

moved forward and backward, as the case may require, in a guide or slide bearing at right angles with the axis of the work-piece or at right angles with the axes of the piercers or centers, for instance E^s , E^9 as shown, 70 such movements being effected by means of the pressure in the pressure cylinder K^{27} , or by any other suitable means. To the said supporting or slide head K^{12} is firmly attached the piston-rod K^{20} of the cylinder K^{27} . 75

The said cylinder K^{27} is firmly bolted to the main bed-plate parts and has a piston with a front piston-rod K^{20} and a rear piston-rod passing through the cylinder 80 heads at both ends of cylinder K^{27} , as more fully shown and described in my said original application. The front piston-rod K^{20} is firmly connected at its outer end with said head K^{12} and near the cylinder end is provided as shown in Fig. 1 with a long thread 85 K^{34} , over which is fitted a threaded adjusting nut K^{36} which is made in halves and firmly held together and to the piston-rod by means of the screws, as shown. The nut K^{36} 90 can be adjusted from one end to the other end of said thread K^{34} , and with the end of the extension K^{22} of the packing box gland forms a stop for the pull-back stroke of the piston in cylinder K^{27} . By adjusting said 95 nut K^{36} forward or backward, as the case may require, the pull-back stroke of the piston in cylinder K^{27} is regulated and thereby the limit of the pull-back movement of the tread or face rolling roll K is adjusted. 100 The rear piston-rod (not shown herein) is firmly fitted and fastened near its end to a cross-head which is similar to the cross-head H^{40} , and from there the piston-rod is provided with a long thread over which is 105 fitted a threaded adjustable nut which is similar to and serves the same purpose as said nut H^{24} and which can be adjusted from one end to the other of the threaded portion of its piston-rod. Said adjustable 110 nut, with the end of the extension of its packing box gland at the outer end of said cylinder K^{27} , forms a stop for the forward stroke of the piston in cylinder K^{27} , and by adjusting said nut forward or backward, 115 as the case may require, the forward stroke of the piston in cylinder K^{27} is regulated and thereby the limit of the forward movement of the tread or face rolling roll K is adjusted; all as more fully shown and 120 described in my said original application.

Said tread or face rolling roll K is connected with the said herein named tread finishing roll H by an equalizing mechanism, 125 for instance, such as shown and described in my said original application and which is adapted to equalize the movements and the pressures of said tread or face rolling roll and said tread or face finishing roll against the work-piece. Said equalizing mechanism 130

may be connected with or be disconnected from said face rolls, for instance K and H, without disconnecting said face rolls from their pressure means; that is, with 5 said equalizing mechanism connected, said tread or face rolls H and K may be moved toward and against or away from the work-piece together, that is, each the same distance. For some rolls or articles it is required that each one of said rolls H and K be moved toward, against, or away from the work-piece independently of each other; or, one of said rolls H and K may be used 10 only, and in such cases, said equalizing mechanism will be disconnected, as for instance shown and described in my said original application. By this means, said tread or face finishing roll H and said tread or face rolling roll K, may be worked, either 15 together or independently of each other.

By the driving means shown and described in my said original application, the roughing side of the apparatus or mill, having the said edging and web rolling roll, 20 may be either connected to or be disconnected from the main driving shaft of the apparatus or mill for the purpose described in my said original application, or may be made to run in either direction, or at such 25 various speeds, as and for the purpose described in my said original application.

Fig. 5 illustrates for instance such rolling or operating process with only such rolls as shown; that is, rolls H, K, J¹ and G¹, together with their operating parts and mechanism are, for instance, the same as the ones shown in Fig. 1 and may also be operated as for instance described with reference to Fig. 1. But in the illustration shown in Fig. 5, the rolls J¹⁰ and G¹¹ together with their operating parts and mechanism shown in Fig. 1 are omitted and in place thereof the work-supporting head M⁵⁰ is provided with the edging and die-supporting rolls 30 for instance X² and X⁴ which, in the illustration shown, turn loose on their journals or spindles and operate as fully described hereinafter with reference to the Figs. 105 to 109 inclusive. In this arrangement, the 35 whole work-supporting head M⁵⁰ together with said rolls, for instance X², X⁴, the forming-die, for instance W²², and the piercer or center, for instance E⁹, may be moved forward or backward and adjusted 40 to their proper positions, as for instance shown in Fig. 5, by the pressure in its pressure cylinder O (see for instance Figs. 6 and 40) the piston of which is operatively connected with said work-supporting head M⁵⁰ and may be adjusted so that the edging roll part g¹³⁷ of said die-supporting roll X² is in contact with said face roll H and, the edging roll part j²⁶ of said edging and die-supporting roll X⁴ is in contact with said face roll K, as shown. At the commencement of

the rolling operation, said face roll K is moved toward and against or in contact with the forming-die W²², as shown in Figs. 5 and 105, and said face roll H is moved a proper radial distance from the axis of said 70 piercers or centers E⁹, E¹⁰. In some cases, said face rolls K and H may be moved toward or against and away from the peripheral face of the work-piece in unison; that is, each face roll will be moved the same 75 distance, or said face rolls K and H may be moved each into a position which is a certain radial distance from the axis of said piercers or centers E⁹, E¹⁰ and be retained in said radial position until the work-piece or 80 wheel is finished, as hereinafter more fully described.

Piercers or work-supporting centers and work-supporting heads, or supporting heads, &c. 85

In Figs. 6, 7 and 8, I have illustrated the device I prefer to use for centering or for piercing or penetrating and centering ingots, blooms, blanks or other work-pieces, 90 for supporting the same, and also for putting the work-pieces at their hubs or center portions while so supported by said work-supporting centers, or by said work-supporting centers and said forming-die, in clamped 95 condition laterally or axially between said piercers or work-supporting centers and automatically keeping said hub or center portion in clamped condition by constant pressure during the rolling and dishing or 100 undishing processes, &c., as hereinafter are fully described and also described in my said original application; said device coacting with the forming-die for such purpose as will be hereinafter described. 105

The herein named work-supporting heads M, M⁵⁰, although so named also serve other purposes, as will be observed from the following:

The work-supporting axle E of said head 110 M has one of said piercers or work-supporting centers at one of its ends, as for instance E⁹, E¹⁰, E¹¹, E¹², &c., and the work-supporting axle E of said head M⁵⁰ has one of said piercers or centers at one of its 115 ends, as for instance, E⁹, E¹⁰, E¹¹, E¹², &c. Said work-supporting heads M, M⁵⁰ are moved longitudinally in line with the axes of said piercers or work-supporting centers by means of the pressures in the cylinders O 120 and N (see for instance Fig. 6) or by any other equivalent means, toward or away from each other; or they may be moved together in either direction; or one of them may be retained in any position while the 125 other is moved toward or away from the one so retained; or they may be moved as the case may require, and as and in the manner hereinafter fully described. One of said work-supporting heads M, M⁵⁰, for instance 130

the head M^{50} , is operatively connected with the piston-rod O^s of the piston in cylinder O and is moved by the pressure in said cylinder. The other work-supporting head 5 M is operatively connected with the piston-rod N^s of the piston in cylinder N and is moved by the pressure in said cylinder.

In Figs. 6, 7, 8, 15 and 16, O is the said pressure cylinder for the work-supporting 10 head M^{50} located at one side of the work-piece or at one side of the forming-die, for instance W^1 ; and, N is the pressure cylinder for the work-supporting head M located at the other side of the work-piece or at the 15 other side of said forming-die W^1 . Cylinder O has a piston with a piston-rod O^s and a piston-rod O^2 passing through both the cylinder heads O^{15} and O^{16} (see Fig. 6) at both ends of cylinder O . The piston-rod 20 O^2 is provided at its outer end with a long thread O^{11} over which is fitted a threaded and adjustable nut O^{12} , as shown. This nut O^{12} can be adjusted from one end to the other of said thread O^{11} . At the outer 25 end of said thread the piston-rod O^2 is provided with a safety stop collar O^{14} which indicates the limit of adjustment of said nut O^{12} toward the end of the piston-rod and thereby prevents the piston from coming 30 against the cylinder head O^{16} . The piston-rod O^s is firmly connected at its outer end with said work-supporting head M^{50} . From the outer end M^{22} of said head M^{50} the piston-rod O^s is provided with a 35 thread over which is fitted a threaded adjustable nut O^r as shown. This nut O^r can be adjusted from one end to the other of said thread, as may be required in adjusting the pull-back stroke of the piston with its 40 rods O^2 , O^s . Next to said nut O^r the piston-rod O^s is also provided with a sleeve or distance piece O^9 as shown (the purpose of this piece O^9 being described in my said original application). The details and 45 description of the cylinder N and its connecting parts for the head M at the other side of the work-piece, are similar to those described above, and the characters of reference N to N^{25} inclusive indicate the corresponding parts O to O^{25} inclusive. In said 50 Figs. 6, 7, 8, 15 and 16, the piercers or work-supporting centers, with their work-supporting heads M^{50} and M are operated by the pressures in said cylinders O and N acting 55 against the pistons of said piston-rods O^2 , O^s and N^2 , N^s in the manner hereinafter described.

In the illustrations shown in Figs. 40 and 41, said head M^{50} with its axle E , piercer 60 or center, for instance E^9 , and forming-die, for instance W^{23} , may be moved into the position for instance shown in Fig. 1 or 5, and therein said head M^{50} and forming-die W^{23} may be retained in a fixed position, 65 and when for instance dishing the work-

piece or wheel, said piercer or center, for instance E^9 , with its axle E is moved axially without moving said head M^{50} , as and in the manner hereinafter described with reference to the Figs. 30 to 41 and Figs. 105 to 70 107, and also with reference to other figures.

Centering, or piercing, or penetrating and centering.

By the words "centering, or piercing or 75 penetrating and centering" used herein, I mean that, the ingot, bloom, blank or other work-piece is centered, or pierced or penetrated by the apparatus or mill, by forcing either one or both of said piercers or work- 80 supporting centers, hereinafter more fully described, against or into the work-piece by their said pressure means (see Figs. 6, 7 and 8), when the outer portion or periphery of said work-piece is brought coaxial, or ap- 85 proximately coaxial, with the piercers or work-supporting centers by means of said positioning, or raising, lowering and retaining device; or metal of the work-piece may be forced over or around any one of 90 said piercers or centers, hereinafter more fully described for instance with reference to Figs. 51, 55, 64, &c.; and this means herein that said work-piece is centered, or pierced or penetrated and centered, because 95 said piercing or penetrating at the same time also centers said work-piece, for the reason that at the beginning of said centering or piercing or penetrating and centering process, the outer portion or periphery 100 of said work-piece is then coaxial, or ap- proximately so, with said piercers or work-supporting centers and is central with the said forming-die; that is, said piercers or work-supporting centers are then in the cen- 105 ter or approximately in the center of the outer portion or periphery of said work-piece.

Centering, or piercing, or penetrating and rolling; and example.

In Figs. 64 and 65, I have for instance illustrated in brief, one of the piercing or penetrating or centering processes or steps and one of the operations for rolling or 110 forming the central or hub portion of a car wheel or other circular body such as I prefer to employ in carrying out the process of rolling or forming car wheels, &c. In Fig. 64, the properly heated blank or work-piece 115 F , shown in diametral section, may have a thickness which is either the same, or greater, or less than the length which the hub of the car wheel or other circular body is to have when rolled to finish. The work-piece F shown in Fig. 64 has been brought into the position shown by a positioning, or raising, lowering and retaining device, such as instance as shown and described in my 120 said original application, in which position 125 130

the outer portion or periphery of the work-piece is coaxial or approximately so with the piercers or work-supporting centers, for instance E^1 , E^9 , and central with the forming-die, for instance W^{12} , and in which position, the work-piece F is pierced or centered, for instance as described in the following: The supporting-head M^{50} with its piercer or center E^9 and forming-die W^{12} and the die-supporting roll G^{14} and the edging and die-supporting roll J^{61} are moved and adjusted into the positions shown, in which positions the flange or shoulder e^{37} of said piercer or center E^9 is against the shoulder formed in said forming-die W^{12} and holds the same against or in contact with the supporting portions of said rolls G^{14} and J^{61} and, the supporting or edging portion g^{187} of said roll G^{14} is in contact with one of the sides of the peripheral face finishing roll H , which roll H is a certain radial distance from the axis of the piercers or centers E^1 , E^9 , as for instance shown and, the edging roll part j^{29} of the edging and die-supporting roll J^{61} is in contact with one of the sides of the face roll K , which roll is in contact with the peripheral edge of said forming-die W^{12} at the commencement of the operation, as shown. In these illustrations, the roll G^{14} , the roll J^{61} , and the forming-die W^{12} are retained in said positions during the operating process, and during the dishing or rolling and dishing processes, said piercer or center E^9 is axially moved or forced into the position shown in Fig. 67 by its power or pressure means operatively connected therewith, as hereinafter more fully described with reference for instance to Figs. 6 to 16 and Figs. 30 to 40. During the actual piercing or penetrating or centering process illustrated in Figs. 64 and 65, the piercer or center E^1 is forced into one side of the work-piece F , while said edging and web rolling roll, for instance J^{69} , formed as shown, rotates or assists in rotating the work-piece together with its forming-die W^{12} and is forced or rolled against and into said side of the work-piece, thus causing the work-piece at its other side to be forced over the other piercer or center E^9 and causing metal of said work-piece to be forced into the hub-forming cavity of the forming-die W^{12} and around said piercer or center E^9 , thus forming the hub at the side of the work-piece adjacent said forming-die W^{12} . During said hub forming process, the end of the roll part j^{43} of said roll J^{69} is either in contact with the peripheral face of said piercer or center E^1 , as for instance shown in Figs. 64 and 65, or comes against said peripheral face of said piercer or center E^1 during the hub forming process and thus rolls or forms the hub at the other side of the work-piece while the work-piece is forced against said forming-die and is rolled or formed to the form shown in Fig. 65. During this process, the roll portion j^{48} of said roll J^{69} operates against the end face of the hub as shown and the edging roll portion j^{29} of said roll J^{69} operates against the portion of the side of the work-piece between the web rolling part j^{28} of said roll J^{69} and the periphery of the work-piece, as shown in Fig. 65. During this operation, the face roll K will operate upon the peripheral face of the work-piece continually and as the work-piece increases in diameter, said face roll K moves with the enlargement of said diameter, while metal in the peripheral portion of the work-piece has been forced over the inclined peripheral face or edge of said forming-die W^{12} and against the edging roll portion j^{29} of said edging and die-supporting roll J^{61} , as shown in Fig. 65. Thus the work-piece is centrally pierced or penetrated or centered and the hub of the work-piece rolled and formed to the desired form and length. Said piercing or penetrating or centering may be done either before or during said hub-rolling or forming process, and said positioning, or raising, lowering and retaining device may be moved away from the work-piece either after or during the piercing or penetrating process. The side of the work-piece next to the forming-die may also be first pierced or penetrated before operation with the rolls, as illustrated for instance in Fig. 43, that is, when the work-piece is in proper position, the piercer or center for instance E^9 is forced into the work-piece, for instance the distance x^7 as shown by the dotted lines, while the forming-die W^1 and the rolls G^{14} , J^{69} , H and K are retained in the positions shown in Fig. 43.

Dishing, undishing and redishing, and a few rolling or forming examples.

In case that all the rolls of the apparatus or mill, that is the rolls of the herein named roughing mill or roughing side of the apparatus or mill and the rolls of the herein named finishing mill or finishing side of the apparatus or mill, are all used for rolling or forming a wheel or other article, as shown for instance in Figs. 6, 7, and 8, the rolling or forming operation against the blank or work-piece having one side against the forming-die may begin with the herein named edging and web rolling roll formed as shown, the edging and die-supporting roll formed as shown, the tread or face rolling roll formed as shown, the forming-die formed as shown, the piercer or center of supporting head M formed as shown, and the piercer or center of supporting head M^{50} formed as shown, and with these parts the blank or other work-piece may be rolled or formed to either of the forms or shapes

- 1, such as shown for instance in any of the Fig. 6, 17, 81, 89, 93 or 95, &c., or similar forms; but in case the finished article should be a dished car wheel having the form or 5 shape shown, for instance, in Fig. 8, the ingot, bloom, blank or other work-piece having been rolled or formed by the herein named edging and web rolling roll, for instance J¹, edging and die-supporting roll, 10 for instance J⁵⁹, the tread or face rolling roll K, the forming-die W¹ formed as shown, the piercers or centers E⁶ and E⁹ formed as shown, to the form or shape F¹ in Fig. 6, and with said rolls and forming-die 15 20 25 30 35 40 45 50 55 60 65 proper distance required for dishing the wheel. With the various parts thus positioned, the dishing may take place, while the work-piece is rotating, in the following manner:—While either, any or all the driven 70 or all the rolls are in operation, and while the said rolls G¹⁴ and J⁵⁹ and forming-die W¹ are retained in fixed rotatable positions, as shown, and with the marginal or rim portion of the work-piece in contact with the 75 forming-die W¹ by reason of pressure being applied thereagainst by, for instance, the roll J¹, the pressure in said cylinder N is gradually somewhat relieved or reduced, retaining therein however, the constant pressure required in said cylinder N to retain the aforesaid automatically axially clamped condition of the hub or center portion of said work-piece between said piercers or work-supporting centers E⁶, E⁹; thereby 80 85 90 95 100 105 110 115 120 125 130 causing the pressure or force from the cylinder O to overcome the resistance of the piston-rod N³ and gradually move the pistons and their rods O², N² and O⁴, N⁴, with their said heads M, M⁵⁰ with the center or hub portion of the work-piece or car wheel axially into the position shown in Fig. 7 while the work-piece or wheel is rotating and the marginal or rim portion of the work-piece or wheel is supported and retained by said forming-die W¹ and said roll J¹, or by said forming-die W¹ and both said rolls J¹ and G¹ against said axial movement of said center or hub portion. In the position and form shown in Fig. 7 at F² the work-piece or wheel is dished as shown, and in this position, if necessary or desired, the rolls may still be in operation against or in contact with the work-piece or wheel, as for instance shown in Fig. 7. It is to be noted that the center or hub portion of the work-piece or car wheel, during this dishing or dishing and rolling process, is firmly held in said automatically clamped condition between said piercers or centers E⁶, E⁹, while said piercers or centers and said forming-die are rotating with the work-piece or wheel.

Instead of so reducing the constant pressure in cylinder N, said dishing can also be done in the same manner, while the work-piece is rotating, by increasing the constant pressure in cylinder O so as to overcome the constant pressure in cylinder N. During the dishing or rolling and dishing operation, the rim of the wheel or other article is supported and retained by the rolls, as shown, which also retain said forming-die W¹ in proper position, as shown in Fig. 6 or 7. In the position shown in the Fig. 7, in which the work-piece or wheel is shown dished, the nut O¹² of the rod O² will now be resting against the end of the gland extension O¹⁷, which forms a stop for this purpose; the sleeve O⁹ will now be away

from the end of the gland extension O^{18} , and the nut N^{12} of the rod N^2 will now be a certain distance, that is the proper distance required for dishing, away from the end of the gland extension N^{17} . After the wheel or other article is completely dished and finished, the rolls may be pulled back, as shown in Fig. 8 and the positioning member of said positioning, or raising, lowering and retaining device located or formed to suit the position of the work-piece or finished wheel F^2 , shown for instance in Fig. 8, is then again raised from its said lower position away from the work-piece to the position adjacent the work-piece; the said piston-rods O^8 , N^8 with their said connected parts are then pulled back into the positions shown for instance in the Fig. 8; thereby placing the finished wheel F^2 or other finished article onto the positioning member of the said raising, lowering and retaining device, and therewith it is then again raised to a position from where said finished wheel F^2 is taken away by any suitable means and another properly heated ingot, bloom, blank or other work-piece put in place of it and lowered and centered, or pierced or penetrated and centered, &c., as above described. In the positions of the parts shown in the Fig. 8, the piston-rods O^2 , O^8 and N^2 , N^8 are pulled back to the adjusted operating limit, for operating under the process above described with reference to the Figs. 6, 7 and 8; that is, the sleeve O^9 is at rest against the end of gland extension O^{18} , forming a stop for this purpose; and the sleeve N^9 is at rest against the end of gland extension N^{18} , which also forms a stop for this purpose.

The dishing operation above described with reference to Figs. 6, 7 and 8 may also be done as illustrated in Figs. 15 and 16 and as shown and described in my said original application; that is to say, when the work-piece has been rolled or formed to the shape shown at F^1 in Fig. 6, as and in the manner above described with reference to said figure, it may be taken out of the apparatus or mill and put into a soaking-pit or heating furnace to retain its proper heat, and the rolls G^1 , J^{59} , piercer or center E^9 and forming-die W^1 will then be removed from the apparatus or mill, and rolls, for instance J^2 , G_2 , and a piercer or center, for instance E^6 , put into the apparatus or mill in place of the removed parts. The work-piece or wheel, while rotating, will then be dished or dished and rolled with the retained and the substitute piercer or center and rolls, as for instance illustrated in Fig. 15. The dishing will be done in a similar manner as above described with reference to Figs. 6 and 7, and also fully described in my said original application. Fig. 16 shows the work-piece freed from all the rolls and

piercers or centers and ready to be removed from the apparatus or mill.

In some work it may be desired to have the pull-back movement or movements of the piston-rod, for instance O^8 , or of both the piston-rods O^8 and N^8 provided each with two or more stops instead of the one described with reference to Figs. 6, 7 and 8, and, in the Figs. 9, 10, 11, 12, 13 and 14, I have for example, illustrated such additional stop or stops for the one piston-rod O^8 , which is the same as the additional stop or stops which may be used for the piston-rod N^8 . Such additional stops will also be required, for instance, in cases wherein one of the piercers or centers is made of certain length to pass through the work-piece and into portion of the other piercer or center, as for instance shown in the Figs. 51 and 55, hereinafter described.

The sleeves O^9 , N^9 are easily exchanged for others, for instance, for shorter sleeves, and they may also be turned on the piston-rods O^8 and N^8 in any desired angular positions; or these sleeves may be entirely removed in cases when such is required. For example, it is only required to exchange for instance the sleeve O^9 shown in Figs. 6, 7 and 8 for a sleeve O^{22} having a moving or sliding or swinging member, for instance member O^{19} which may have any thickness, such as may be required in other cases or which may be made in sections of which each has a predetermined thickness. Said sleeve O^{22} may be shorter than sleeve O^9 , and it is formed with an arm provided with a removably fitted pivot or bolt O^{20} and a pin O^{21} . When the member O^{19} is to be of a different thickness than that shown in the drawing, said pivot or bolt O^{20} may be exchanged for another which will suit the thickness of said member. Said member O^{19} is formed, as shown in Fig. 14, with a slot O^{24} opening at the edge thereof and fitting loosely over the piston-rod O^8 and it is provided with a bearing or hole to fit on said pivot O^{20} , as shown. In Fig. 13, which is a cross-section of Fig. 9 through line 13—13 looking in the direction of the arrows, is shown the piston-rod O^8 in section, the sleeve O^{22} in end view, and said member O^{19} mounted on its pivot O^{20} . Said member O^{19} is also provided, in this example, with an extension or part O^{22} having a hole O^{25} permitting connection of a lever or levers thereto for moving or swinging the same in or out of operative position. In the Figs. 9, 10 and 13, said member O^{19} is shown in operative position; in Fig. 11 it is shown in inoperative position, and in Fig. 13 it is so shown in dotted lines in inoperative position. The pin O^{21} serves as a stop for the swinging movement of said member O^{19} when moving the same out of operative position, as shown in Figs. 11 and 13. It is,

of course, to be understood that said members O^{19} and N^{19} may have any thickness and any suitable form or forms, or each member O^{19} may consist of two or more sections of which each may have a predetermined thickness to suit the various purposes herein described, or as may be required.

For example; in the operating process described with reference to Figs. 6 to 11 inclusive, said sleeve O^{22} and member O^{19} are substituted for said sleeve O^9 and, with the member O^{19} in operative position as shown in the Figs. 9 and 10, the total length of said sleeve O^{22} together with the member O^{19} may be the same as the length of sleeve O^9 . When using the sleeve O^{22} with its member O^{19} , instead of the sleeve O^9 , the operation may be the same or similar to the operation described with reference to Figs. 6 and 7; but, it may be desired in some cases, for instance, that the head M^{50} together with its piercer or center, for instance E^9 , and forming-die, for instance W^1 , and also the rolls, for instance J^{50} and G^{14} , be pulled back to the positions thereof shown, for instance, in Fig. 12; that is, to a greater extent than that shown in Fig. 8; in which case it will only be required to move said member O^{19} out of operative position into the position thereof shown in Fig. 11, which will permit said parts M^{50} , E^9 , W^1 , J^{50} and G^{14} to be pulled back the additional distance, for instance x^8 , (see Figs. 8 and 11) which is equivalent to the thickness of said member O^{19} , and the wheel F^2 , when ready to be removed, will be in the position shown thereof in Fig. 12; and, in this operation the head M , center E^9 and rolls J^1 , G^1 will only be pulled back to the positions thereof shown in Fig. 12.

With reference to Fig. 51, wherein is shown the axle E of the supporting head M^{50} provided with a piercer or center, for instance E^{14} having a cylindrical portion e^{37} slidably fitted in the central bore of the forming-die W^6 , a tapered portion e^{39} on which the work-piece F with its central hole is adapted to be supported, and a cylindrical portion e^{40} slidably fitted into the central hole or bore e^{41} of the center E^{13} of the other supporting head M , as shown. When the work-piece F in Fig. 51 is put into the apparatus or mill, the supporting head M^{50} together with its axle E and piercer or center E^{14} will be longitudinally moved from its position shown in solid lines to the position thereof shown in dotted lines, that is, the distance for instance indicated by x^8 . In this case said sliding or swinging member O^{19} (see Figs. 9, 10 and 11) will be given a thickness equivalent to said distance x^8 , or said member O^{19} may be made of two parts having a total thickness equivalent to said distance x^8 and of which two parts the part adjacent or near the said part O^{18} of

cylinder O has the same thickness as O^{19} shown in Figs. 9, 10 and 11, and the sleeve O^{22} will be given a length so that the total thickness of the two parts of said member O^{19} together with the sleeve O^{22} will have 70 a thickness or total length which is equivalent to the length of said sleeve O^9 . With the piston-rod O^8 thus provided with said two-part member O^{19} and sleeve O^{22} , the operation will be thus:—Said two-part member O^{19} will be moved out of operative position and the piston-rod O^8 will then be moved or pulled back until said sleeve O^{22} will rest against said part O^{18} of cylinder O which will have moved the piercer or center 80 E^{14} into the position shown in the dotted lines in Fig. 51, and when the work-piece is brought into the position shown in Fig. 51, said piston-rod O^8 will again be moved forward the distance indicated by x^8 in Fig. 85 51 and the said two-part member O^{19} moved into operative position wherein said one part of said two-part member O^{19} , that is, the one having the same thickness as the member O^{19} shown in Figs. 6 to 11, will be 90 against said part O^{18} and, said supporting head M^{50} together with its axle E and piercer or center E^{14} be again in the position shown in Fig. 51, and the operating process for dishing the wheel after the 95 work-piece has been rolled or formed to the form shown at F^1 in Fig. 53 will be similar to operating process above described with reference to Figs. 6 to 10 inclusive; and if so desired, the one part of said two-part member O^{19} , that is, the one adjacent said part O^{18} having the same thickness as the member O^{19} shown in said Figs. 9, 10 and 11, may be moved out of operative position, the same as shown in Fig. 11, and for the 100 same or similar purpose described for Figs. 105. 8, 11 and 12. When the work-piece or wheel is ready to be removed, said member O^{19} will again be moved out of operative position and said supporting head M^{50} with its axle E and piercer or center E^{14} will be pulled back into the position shown in dotted lines in said Fig. 51 and a new blank or other work-piece put into the apparatus or mill as and in the manner above described. 110

With reference to Fig. 55, wherein is shown the axle E of the supporting head M provided with a piercer or center for instance E^{15} having adjacent its axle end a 120 cylindrical or slightly tapered portion e^{42} and next thereto a tapered portion e^{39} on which the work-piece F with its central hole is adapted to be supported and, at the small diameter of said tapered portion e^{39} said piercer or center is formed with a shoulder as shown. From said shoulder said piercer or center is formed with a cylindrical portion e^{43} fitted into the central hole or bore e^{44} of the center E^{16} of the 125 130

other supporting head M^{50} , and with its said shoulder said piercer or center E^{15} is acting against or in contact with said other center E^{16} , as shown. When the work-piece F in 5 Fig. 55 is put into the apparatus or mill, the supporting head M together with its axle E and piercer or center E^{15} will be longitudinally moved from their positions shown in solid lines to the positions thereof shown 10 in the dotted lines, that is, the distance for distance indicated by x^o . In this case, the sleeve N^o on the piston-rod N^s of the cylinder N will be exchanged for sleeve N^{22} and member N^{19} , similar to the corresponding 15 parts O^{22} and O^{19} of the piston-rod O^s , and said sliding or swinging member N^{19} will be given a thickness equivalent to said distance x^o . The said member N^{19} together with said sleeve N^{22} will have a thickness or 20 total length which is equivalent to the length of said sleeve N^o . With the piston-rod N^s thus provided with said member N^{19} and sleeve N^{22} , the operation will be thus: Said member N^{19} will be moved out of operative 25 position, and the piston-rod N^s will then be moved or pulled back until said sleeve N^{22} will rest against said part N^{18} of cylinder N, which will have moved the piercer or center E^{15} into the position shown by the 30 dotted lines in Fig. 55, and when the work-piece is then brought into the position shown in Fig. 55, said piston-rod N^s will be moved forward again the distance for distance indicated by x^o in Fig. 55, and the 35 said member N^{19} moved into operative position, wherein it will be against said part N^{18} (see Figs. 6 to 11), and said supporting head M together with its said axle E and piercer or center E^{15} will again be in the position 40 shown in Fig. 55. The operating process for dishing the work-piece or wheel, after the work-piece has been rolled or formed to the form of an undished wheel, will be similar to the operating process 45 above described with reference to Figs. 6, 7 and 8, or to the Figs. 6 to 10 inclusive; and, if so desired, the parts O^{19} and O^{22} for the piston-rod O^s of the cylinder O may be used as described with reference to Figs. 9, 50 10, 11 and 12. When the work-piece or wheel is ready to be removed, said member N^{19} will again be moved out of operative position and said supporting head M with its axle E and piercer or center E^{15} will be 55 pulled back into the position shown in dotted lines in said Fig. 55 and a new work-piece put into the apparatus or mill as and in the manner above described.

In Figs. 17 to 24 inclusive, the pressure 60 cylinders O and N with their rods, shown in the Figs. 6 to 11 inclusive, are omitted and only parts of the work-supporting heads M, M^{50} are shown with their axles E, E and piercers or work-supporting centers, 65 for instance E^s , E^o and the forming-die for

instance W^1 , with different arrangements and forms of rolls. In these figures, the operations for putting in the ingot, bloom, blank or other work-piece and removing the finished article and for centering or for 70 piercing or penetrating and centering the ingot, bloom, blank or other work-piece and for dishing the wheel or other article, are also similar to those described for and illustrated by said Figs. 6 to 11 inclusive. In 75 case that, the article which may be desired to be rolled or formed and dished by only such rolls as are shown in the said Figs. 17 to 24 inclusive, then in such case, the rolls not shown in these Figs. 17 to 24 inclusive, 80 will not be used in the rolling or rolling and dishing of such article, and therefore may be omitted; or an apparatus or mill may be made without them. For instance; a wheel or other article is to be rolled or formed 85 and dished with only the rolls shown in Figs. 17 and 18; and the dishing done with the same parts while either, any, or all the driven rolls or all the rolls shown in said Figs. 17 and 18 are in operation and done, 90 while the work-piece is rotating, in the same manner as before described with reference for instance to Figs. 6 to 11 inclusive, and in this case, Fig. 17 shows for instance, a car wheel ingot, bloom, blank or work-piece 95 centered or pierced or penetrated and centered as before described and rolled or formed on piercers or work-supporting centers, for instance E^s , E^o and on a forming-die, for instance W^1 , with the herein named 100 edging and web rolling roll, for instance J^1 , edging and die-supporting roll for instance J^{50} and tread or face rolling roll K, to the shape F^1 shown in the Fig. 17. Fig. 18 shows said work-piece F^1 rolled or formed, 105 dished and finished to the form or shape of the car wheel, F^2 , as shown. During the dishing, or rolling or forming and dishing process, the rim of this wheel or other article, is sufficiently supported and retained by 110 the forming-die W^1 and by the said rolls J^1 , J^{50} and K, as shown, and the dishing process is the same as before described with reference to and illustrated in Figs. 6 to 11 inclusive. A wheel or other article may be 115 rolled or formed and dished for instance, with only the rolls shown in Figs. 19 and 20, and the dishing done with the same parts while either, any or all the driven rolls, or all the rolls shown in said Figs. 19 and 20 120 are in operation and done, while the work-piece is rotating, in the same manner as before described with reference for instance to the Figs. 6 to 11 inclusive, and in this case, Fig. 19 shows, for instance, a car wheel ingot, bloom, blank or work-piece, centered or pierced or penetrated and centered as before described and rolled or formed on piercers or work-supporting centers for instance E^s , E^o and on forming-die, for in- 125 130

stance W^1 , with the herein named edging and web rolling roll, for instance J^1 , edging and die-supporting roll, for instance J^{14} , tread or face rolling roll K and the herein 5 named tread or face finishing roll H , to the form or shape F^1 shown in the Fig. 19; and Fig. 20 shows said work-piece F^1 rolled or formed, dished and finished to the form or shape of the car wheel F^2 , as shown. During 10 the dishing, or rolling or forming and dishing process, the rim of this wheel or other article is sufficiently supported and retained by the forming-die W^1 and by said rolls J^1 , J^{14} and K , as shown; and the dishing 15 process is the same as before described with reference to and illustrated in Figs. 6 to 11 inclusive.

An ingot, bloom, blank or work-piece is shown in Fig. 21 having the form or shape, 20 for instance shown at F . This ingot, bloom, blank or work-piece is to be rolled or formed only at its rim, tread and flange, and at part of the web next to the rim, and it is to be dished and rolled or formed with only the 25 use of the rolls shown in Figs. 21 and 22; and the dishing done with the same parts while either, any, or all the driven rolls, or all the rolls shown in said Figs. 21 and 22 are in operation and done while the work- 30 piece is rotating in the same manner as before described with reference for instance to Figs. 6 to 11 inclusive, and in this case, Fig. 21 shows, for instance, such ingot, bloom, blank or other work-piece having, 35 for instance, form or shape shown at F , and having been centered or pierced or penetrated and centered as before described and ready to be rolled or formed on piercers or work-supporting centers, for instance E^a , E^p and on the forming-die, for 40 instance W^1 , with only the herein named web finishing roll, for instance G^1 , die-supporting roll for instance G^{14} , and tread or face roll H , to the form or shape F^2 before 45 dished in the Fig. 22, and Fig. 22 shows said ingot, bloom, blank or work-piece rolled or formed, dished and finished to the form or shape of the car wheel F^2 shown in the Fig. 22. During the dishing, or rolling or 50 forming and dishing process, the rim of this wheel or other article is sufficiently supported and retained by the forming-die, for instance W^1 , and by the rolls G^1 , G^{14} and H , as shown, and the dishing process is the 55 same as before described with reference to and illustrated in Figs. 6 to 11 inclusive. A car wheel blank, ingot, bloom or work-piece is shown in Fig. 23 having the form or shape, for instance, as shown at F . This 60 blank, ingot, bloom or work-piece is to be rolled or formed only at its rim, tread and flange and at part of the web next to the rim and it is to be dished and rolled or formed with only the use of the rolls shown 65 in the Figs. 23 and 24, and the dishing done

with the same parts and while either, any or all the driven rolls or all the rolls shown in said Figs. 23 and 24 are in operation and done, while the work-piece is rotating, in the same manner as before described with reference 70 for instance to Figs. 6 to 11 inclusive, and in this case, Fig. 23 shows for instance, such car wheel blank, ingot, bloom, or work-piece having for instance the form or shape shown at F , and having been centered or 75 pierced or penetrated and centered as before described and ready to be rolled or formed on piercers or work-supporting centers, for instance E^a , E^p and on the forming-die, for instance W^1 , with only the use of the herein 80 named web finishing roll, for instance G^1 , die-supporting roll, for instance G^{14} , tread or face finishing roll H , edging and web rolling roll, for instance J^1 , and the edging 85 and die-supporting roll for instance J^{14} , said roll J^1 having the shape as shown (in this case, such roll as J^1 may either be driven by its shaft J or it may be turning loose on a bearing attached to the end of said shaft J , and the edging and die-supporting roll, for 90 instance J^{14} , may either be wholly driven by its shaft or be partly driven by its shaft J , and the other part or parts be in sections which are permitted to turn loose on a bearing or bearings provided therefor and 95 which bearing or bearings are attached to the end of said shaft J), to the form or shape F^2 before dished in the Fig. 24; and, Fig. 24 shows said car wheel blank F rolled or formed, dished and finished to the form 100 or shape of the car wheel F^2 . During the dishing, or rolling or forming and dishing process the rim of this wheel or other article is sufficiently supported and retained by the forming-die, for instance W^1 , and by 105 the rolls G^1 , G^{14} , H and J^1 , J^{14} , as shown, and the dishing process is the same as before described with reference to Figs. 6 to 11 inclusive.

From the foregoing it will now be observed that, the piercers or work-supporting centers, together with the forming-die, revolvably or rotatably support the work-piece and that with the constant pressures in said cylinders N and O being operatively connected with said piercers or work-supporting centers by the means before described, and also shown and described in my said original application, said piercers or work-supporting centers are pressed or forced automatically by constant pressures in said cylinders toward and against each other or toward and against the opposite ends of the hub or against the opposite sides of the center portion of the work-piece, or as and in 110 the manner herein shown and described. In this manner the work-piece or wheel, while so supported by said piercers or work-supporting centers at its hub or center portion, is also automatically put into clamped con- 115 120 125 130

- dition laterally or axially at said hub portion between said piercers or work-supporting centers. Said automatic and constant pressure also serves other purposes, as and in the manner hereinafter described. For instance, by constant pressures in said cylinders, the hub or center portion of the work-piece or wheel is also automatically and firmly clamped laterally or axially between 5 said piercers or work-supporting centers, which is absolutely necessary in order to prevent said hub or center portion from being forced out of its true axial or central and desired lateral positions with respect to 10 the remainder of the work-piece or wheel, during the dishing or undishing, or the rolling and dishing or undishing processes, &c., and this said constant clamping force or constant clamping pressure automatically 15 20 and continually remains during said processes and automatically retains the hub or center portion of said work-piece in its true axial or central position during any desired axial or lateral movement, for instance, of 25 the work-piece together with the forming-die, or of the hub or center portion of the work-piece or wheel during either of said processes. While the work-piece or wheel is so supported by said forming-die and by 30 35 40 45 50 55 60 65 70 75 80 85 90 95 100 105 110 115 120 125 130 said piercers or work-supporting centers and is also so automatically and firmly clamped laterally or axially at its hub or center portion, said work-piece together with the forming-die, or the hub or center portion of the work-piece may be so automatically moved axially with its said piercers or work-supporting centers, while the marginal or rim portion of the work-piece is laterally supported and retained by said forming-die and said rolls during either of said processes, as may be desired, or as hereinafter shown and described; and, to cause said automatic axial movement during the operation while the work-piece or wheel at its hub or center portion in automatically clamped condition is dished, or undished, or rolled and dished or undished, or adjusted between the rolls, &c., or for instance as hereinafter shown and described, it will only be required that, either the constant pressure in only one of said cylinders N or O is gradually somewhat reduced so as to cause said automatic axial movement as desired and as before described; or, the constant pressure in only one of said cylinders N or O is gradually somewhat increased so as to overcome the pressure in the other cylinder and thereby cause said automatic axial movement as desired. 70 75 80 85 90 95 100 105 110 115 120 125 130 This dishing, undishing or reddishing operation may also be effected by retaining said work-supporting axles or work-supporting means in fixed rotatable positions while the work-piece is rotating and is so 65 70 75 80 85 90 95 100 105 110 115 120 125 130 rotatably supported at its center or hub portion by said work-supporting means and is so laterally or axially clamped between said work-supporting means, as and in the manner before described, and by moving the rolls for instance J¹, J², forming-die for instance W¹, and roll K in a lateral direction while the same are positioned for instance as in Fig. 17, or similar thereto, and while the same, or at least the rolls J¹, J² and forming-die W¹ are kept in contact with the marginal or rim portion of the work-piece. In thus applying my invention for dishing, the marginal or rim portion of the work-piece together with the forming-die W¹, are moved laterally or axially with respect to its central portion; or, for producing the same effect, both said central work-supporting means and said rolls together with the forming-die may be moved in opposite directions parallel with the axis of the supported work-piece, while said work-piece at its center or hub portion is so supported and is so laterally or axially clamped and while said roll J¹ is kept in contact with one side of the marginal or rim portion and said roll J² is kept in contact with the forming-die W¹ and also in contact with the other side of the marginal or rim portion of the work-piece, as shown for instance in Fig. 17. Undishing and reddishing may be done in a manner similar to the dishing. In undishing, the dished object is placed partly on the forming-die and partly on said work-supporting centers, as for instance shown in Fig. 67, and while so supported, both the piercers or centers for instance E¹, E², are moved axially until the work-piece or wheel is undished, as for instance shown in Fig. 66. In a dished wheel, the web, that is the part of a wheel between the hub part and the rim part, is in an inclined position, as for instance shown in the wheel F² in Fig. 76, and in an undished wheel the web is in a straight position, that is, at right angles with the axis of the wheel, or approximately so, as for instance shown in the undished finished wheel F², in the Fig. 78. On this account, the said web is longer in the said dished position than in the said undished or straight position, and, the extra length or difference between the length of the web of a dished and undished wheel has to be made up during the dishing process. For example, in case that a wheel has been finished by any means to the form or shape shown, for instance, at F² in Fig. 78, and, such wheel is to be dished to the form or shape shown, for instance, at F² in Fig. 76, and, in case such dishing would have to be done, for instance, in the usual manner or through pressure in dies, then in such dishing process, the said web would have to be lengthened by direct extension of the metal in the web in the direction

from the hub to the rim part, or vice versa. Under such methods, an immense force is required to do such dishing, and during such dishing process it will also be possible to twist the finished rim part with its tread and flange and cause the wheel to be untrue and out of gage. All such difficulties are prevented with my method for dishing or for rolling and dishing, and the force or power required to do the dishing with my process will be very little, as can be easily observed from the following:—With reference to the Figs. 66 and 67 for instance; Fig. 66 illustrates an ingot, bloom, blank or other work-piece rolled or formed with the rolls, for instance J^{*1} , J^{*2} , forming-die, for instance W^{*2} , and face roll K to the undished form or shape F^1 shown in Fig. 66; then with the rolls J^{*1} , J^{*2} still in operation, the herein named finishing rolls, for instance G^1 and H commence operating against the wheel, and the dishing may be commenced at the same time and in the manner before described, and when completely rolled and dished to the form F^2 in Fig. 67, the rolls J^{*1} , J^{*2} , G^1 and H , in the positions for instance shown in Fig. 67, may still operate against the wheel, whereby the wheel is made perfectly true and to balance, also to gage or gages. The said necessary lengthening of the web is performed during the dishing process with the herein named web finishing roll, for instance G^1 , as shown for instance in the Fig. 67 and other figures, by rolling out the metal j near the inner rim part at one side of the work-piece or wheel as indicated by the clearance between said inner rim part of the wheel and the web reducing roll part j^{*2} of the said roll J^{*2} , which metal was left there by said web reducing roll part j^{*2} of the herein named edging and web rolling roll, for instance J^{*2} , as shown; and thereby adding during the rolling and dishing process, by my method of dishing or rolling and dishing, sufficient metal to the web part and providing thereby the required metal for the said extra length to the web part, without producing such above described direct tension in the web.

With reference to Figs. 25, 26, 27, 28 and 29 shown on an enlarged scale; Fig. 25 shows the work-piece rolled or formed and dished as before described with reference to Figs. 6 to 12 and as hereinafter more fully shown and described. In this Fig. 25 the work-piece or wheel F^2 and forming-die W^1 are shown in diametral sections, and the opposite end parts of the alined supporting heads M^{*0} , M are shown in side elevation, the end portions of the rolls G^{*1} and G^1 being also shown. Said parts F^2 , W^1 , G^{*1} , M^{*0} , G^1 and M in this Fig. 25 are shown in the positions they occupy at the end of the rolling or forming and dishing.

operations, the wheel F^2 being shown finished and ready to be removed. In said Fig. 25 are also shown parts of the alined guides M^{*1} , M^{*1} for said supporting heads M^{*0} , M , and the portions of the bed-plate B^2 , B^2 to which said guides M^{*1} , M^{*1} are fixedly secured; and the arrows M^1 , M^0 designate the inlet flow of the cooling medium into the cooling medium reservoirs M^{*1} , M^{*1} of said heads M^{*0} , M ; and M^{*1} , M^{*1} the opening or outlet through which the cooling medium flows and from which it is directed over said heads, as hereinafter described with reference to Figs. 39, 40 and 106, and as and for the purpose more fully shown and described in my said original application.

Fig. 26 shows the work-piece rolled or formed to the form of an undished wheel shown at F^2 and rolled or formed as hereinafter more fully described. In this Fig. 26 the work-piece or wheel F^2 and forming-die, for instance W^1 , are shown in diametral sections, and the opposite end parts of said alined supporting heads M^{*0} , M are shown in side elevation; the end portions of the rolls G^{*1} and G^1 being also shown. Said parts F^2 , W^1 , G^{*1} , M^{*0} , G^1 and M in this Fig. 26 are shown in the positions they occupy at the end of rolling or forming operation; the undished wheel F^2 being shown finished in undished form and ready to be removed. In this figure are also shown loose supporting rolls X^1 , X^1 which support the forming-die, for instance W^1 , as shown. These supporting rollers (see also Figs. 27 and 28) are for instance journaled in bearings x^1 , x^2 , &c., and are adjustably supported in brackets x^1 , x^2 which are bolted or fastened to the supporting head M^{*0} , as shown. The portions of each of said brackets fitted with said bearings x^1 , x^2 are open or fork-shaped to receive said bearings and between each of said bearings x^1 , x^2 and the inner end of the fork-shaped portion of said bracket is inserted a plate or plates x^4 having the proper thickness to keep said roll X^1 against or in contact with the forming-die W^1 , as shown. This plate, or plates, x^4 can be exchanged for plates of any thickness required to keep said roll X^1 against or in proper contact with said forming-die. In this manner, said rolls X^1 , X^1 are adjustably mounted so that they may properly engage the forming-die.

In Fig. 29 is shown the end part of an enlarged horizontal section through the water cooling or other cooling medium arrangement for the work-supporting axle of one of my said work-supporting heads M^{*0} , M ; that is, of the supporting head M . The cooling medium enters the pipe e^{*1} at one end thereof (not shown herein, but fully shown and described in my said original application), passes through said pipe in

the direction of arrow e^{14} and out of said pipe into the annular space e^3 formed by said pipe e^{11} and the inner bore of the axle E and in the direction of the arrows e^{15} and out of said first-mentioned end, not shown herein; thereby cooling the axle E during the operating process and also said piercers or centers, for instance E^6 , or lowering the temperature thereof. Said piercers or centers, as for instance E^6 , are exchangeable for other formed piercers or centers or forming-dies, as hereinafter shown and described, and they are preferably fastened to the axle E in such a way that they may readily be exchanged for others, as for instance by the means of pins e^1 , e^1 , shown in Fig. 29, or by any other desirable means. Each of said axles E, E^6 may have its end E^7 made to any length, such as may be required or desired and as hereinafter described.

With the supporting rollers X^1 , X^1 as arranged in Fig. 26, or with the arrangement of the rolls X^3 and X^4 supported and carried by the supporting head M^{50} in Fig. 5 and shown in detail in the Figs. 105 to 107 inclusive, the dishing will be done for instance in the following manner: With reference to Fig. 5 and Figs. 105 to 107 inclusive, the supporting head M^{50} , supporting-die, for instance W^{22} , edging and supporting rollers X^3 , X^4 are brought into the positions shown for instance in Fig. 5 and will be retained in the said positions during the dishing or dishing and rolling process while the axle E with its piercer or center E^6 is moved or forced by the pressure in the pressure cylinder U operatively connected therewith, as hereinafter shown and described with reference to the Figs. 30 and 41.

Device for moving the piercer or center independent of the supporting head, or for moving the supporting head together with the piercer or center.

With reference to the Figs. 30 to 41 inclusive, illustrating on enlarged scale the hereinbefore-mentioned device for longitudinally moving or operating one of the supporting axles E, E^6 and its piercer or center, for instance E^6 , independent of its supporting head M^{50} , or for moving said supporting head M^{50} together with said axle E and piercer or center E^6 :

Fig. 30 is a horizontal section through line 30—30, Fig. 32, and shows the axle E and, supporting head M^{50} including the water cooling or other cooling arrangement for cooling the axle E, for the purposes described in my said original application. The supporting head M in Fig. 6 is provided at the outer end M^{52} of its upper portion with an end plate M^1 , and the parts connected therewith are as shown and de-

scribed in my said original application, and, the supporting head M^{50} in Fig. 6 may be provided at the outer end M^{52} of its upper portion with said end plate M^1 , or said head M^{50} may be provided at the outer end M^{52} 70 of its upper portion with the end plate U^{31} and the parts connected therewith as shown for instance in said Figs. 30, 31 and 40.

With reference to Figs. 30 to 41 inclusive; said parts M^{50} and U^{31} also form the supports for the bearings M^3 , M^4 and M^5 for the herein named work-supporting axle E. Said end plate U^{31} also supports with its inner end, as shown in Fig. 30, the combined cross-head and ball race-way U^{51} forming 80 part of the mechanism for causing the longitudinal movements of the supporting axle E; that is to say, when the supporting head M^{50} and axle E are moved together or in unison, said part M^{51} is at all times held 85 with one side against said end plate U^{31} (see Fig. 30) by the keys U^{17} , of which one is shown in Figs. 33 and 34, which keys will then be inserted into the key-holes U^{18} of the operating rods U^{15} and thus lock the 90 axle E against longitudinal movement independently of the supporting head M^{50} , as will be seen from said Fig. 30. With said keys U^{17} inserted in said key-holes U^{18} , the axle E will then be moved longitudinally 95 together with the supporting head M^{50} . When, however, the said keys are not inserted in their said key-holes, the axle E is unlocked and will be moved forward and backward independently of the supporting 100 head M^{50} by the pressure in the cylinder U (see Fig. 40) acting upon a piston in said cylinder and rod U^2 operatively connected with the operating rods U^{15} , (or by any other equivalent means); that is to say, the 105 supporting head M^{50} may be retained in the position shown in Figs. 30 and 31 and the axle E and piercer or center, for instance E^6 , moved forward and backward independently of the supporting head M^{50} , by 110 the pressure in cylinder U (see Fig. 40) acting upon a piston in said cylinder and the rod U^2 operatively connected with said operating rods U^{15} , for instance the distance x^7 , from its position shown in Fig. 30 to its position shown in Fig. 31. In this latter position of said axle E and piercer or center, for instance E^6 , said combined cross-head and ball race-way M^{51} will be away from 115 said end plate U^{31} the distance x^7 as shown 120 in Fig. 31. To the ends of said operating rods U^{15} is firmly attached or fastened, as shown, the cross-head U^{30} . To said cross-head U^{30} is removably but firmly attached, by means of nut U^{12} , the shouldered end of 125 the piston-rod U^2 as for instance shown in Figs. 30, 31 and 40. Said piston-rod U^2 has a piston operating under pressure in the cylinder U (see Figs. 40 and 41) and another piston-rod U^1 . Said piston-rods U^2 130

and U^1 pass through the cylinder heads U^4 and U^5 at opposite ends of cylinder U . Next to said cross-head U^{30} , said piston-rod U^2 is provided with a long thread, as shown, over 5 which is fitted a threaded and adjustable nut U^{11} (see Fig. 40), as shown. This nut U^{11} can be adjusted from one end to the other of said thread, as may be required in adjusting the pull-back stroke of the piston 10 ton with its rods U^2 and U^1 . Said piston-rod U^1 is provided at its outer end with a long thread U^5 over which is fitted a threaded and adjustable nut U^8 , as shown in Fig. 40. This nut U^8 can be adjusted from one 15 end to the other of said thread U^5 , as may be required in adjusting the forward stroke of the piston with its rods U^2 and U^1 . At the outer end of said thread a safety stop collar U^9 is provided which indicates the 20 limit of adjustment of said nut U^8 toward the end of the piston-rod and thereby prevents the piston from coming against the cylinder head U^4 . Next to said nut U^{11} , the piston-rod U^2 is also provided with a sleeve 25 or distance piece U^{10} as shown. Said sleeve U^{10} may be made shorter and fitted with a member as or similar to member O^{19} hereinbefore described with reference to Figs. 9, 10, 11, 13 and 14, or said sleeve U^{10} may be 30 made shorter to permit a greater longitudinal movement of said axle E , if desired. The sleeve U^{10} and nut U^{11} , are removed from the piston-rod U^2 to permit said piston-rods U^2 and U^1 to be entirely disconnected from 35 said cross-head U^{30} and be moved out of operative position, as for instance shown by the dotted lines in Fig. 40. When the piston-rod U^2 is so disconnected, the keys U^{17} are inserted into the key-holes U^{18} and, with 40 said axle E in the position shown in Fig. 30 and with said keys U^{17} inserted into said key-holes U^{18} , said axle E and piercer or center, for instance E^9 , will be moved longitudinally or operated together with said 45 supporting head M^{50} ; and, said supporting head M^{50} will then be operated by the pressure in said cylinder O acting against the piston and piston-rods O^3 and O^2 operatively connected to said supporting head M^{50} , as 50 and in the manner hereinbefore described with reference to Figs. 6 to 11 inclusive, and also as shown and described in my said original application. The lower end of the casting for said cylinders U and O is rigidly 55 fastened to the bed-plate portion B^2 in Fig. 40, and said supporting head M^{50} is slidably supported and guided in the guide M^{51} which is fastened to said bed-plate portion B^2 , as for instance shown in said Fig. 40, 60 partly illustrated in the Fig. 25, and more fully shown and described in my said original application. Between the inner end of the enlarged bore of said supporting head M^{50} and its end plate U^{51} (see Figs. 30 and 65 31), the supporting axle E is partly enlarged in diameter to form a flange or shoulder E^{20} , as shown, over and against which flange or shoulder is fitted the other ball race-way or ball pressure plate M^7 . Between these two parts M^{51} and M^7 are placed the balls 70 M^8 , sufficiently large in diameter and sufficient in number to safely resist the pressure during the centering, or piercing or penetrating process of the ingots, blooms, blanks or other work-pieces, and during said 75 clamping process of said work-pieces at their central or hub portion between said piercers or centers, and during the dishing process of the wheel or other article. The distance between the inner shoulder or inner end of the 80 enlarged bore of said supporting head M^{50} and the end plate U^{51} may be made greater to suit any desired movement of said axle E and the other parts of the mechanism connected with said movement may be made to 85 suite such greater movement of said axle E .

The axle E , for instance of the supporting head M^{50} , has at its outer end one of said piercers or centers, for instance E^9 (see Figs. 30 and 31), on which is mounted said 90 forming-die, for instance W^{23} as illustrated in Fig. 40 and as hereinafter more fully shown and described. The axle E , for instance of the supporting head M in Fig. 1, has one of said piercers or centers, for instance E^6 , and the axle E , of the supporting head M in Fig. 64, has one of said piercers or centers, for instance E^1 , all as hereinafter 95 more fully shown and described. Each of said axles E , E is provided with a central 100 bore which extends from one end to a point near its other end, as shown herein, and also as shown and described in my said original application.

With reference to Figs. 30 and 31, the 105 axle E is reduced in diameter adjacent said part M^{51} to form shoulders thereon next to said part M^{51} and at the flange or collar e^{48} adjoining the retainer collar U^{14} , as shown. Between said two shoulders the axle E is 110 provided with a feather U^{13} (see Fig. 30), and said retainer collar, which is made in halves and provided with a key-way U^{19} , as shown in Figs. 35 and 36, is placed over the axle E between said two shoulders so that 115 said key-way U^{19} is over said feather U^{13} . Said retainer collar U^{14} thus forms a part of said axle and is rotated therewith and with its outer peripheral face forms a journal for said bearing M^5 . When said axle 120 E is moved longitudinally independent of said head M^{50} , said retainer collar is also moved with said axle. The object of this retainer collar U^{14} is to form a part of the axle which part must be taken off and again 125 put onto the axle when disassembling the parts of the device and when assembling or putting the device together, and also to retain said ball-bearing parts M^7 , M^8 and M^{51} in their proper positions between said 130

flange or shoulder E^{20} and said retainer collar U^{14} . Said retainer collar U^{14} bears with one end against said part U^{51} and with its other end it is firmly held in place by the shoulder e^{18} of said axle E . The axle E is therefore moved longitudinally or pulled back through the medium of said part M^{51} , which is operated forward and backward by the pressure in said cylinder U acting upon the piston and its rod U^2 , which rod is operatively connected with said part M^{51} by said parts U^{20} and U^{15} , as shown in Figs. 30, 31 and 40. To put the retainer collar U^{14} into its place on the axle it must be made for instance in half, as shown. In putting the device shown in Figs. 30 and 31 together; the axle E with the parts M^7 , M^8 , M^{51} and with the retainer collar U^{14} in its place on the axle, are put into the supporting head M^{50} and the end plate U^{31} is then put into its place as shown and the other parts put into their proper places, as shown; after which the desired form of piercer or center, for instance E^9 , is put onto the end of the axle, as shown.

When sleeve U^{10} and nut U^{11} are removed from said piston-rod U^2 , and said piston-rod is disconnected from said cross-head U^{20} and moved with the piston-rod U^1 into inoperative position, as for instance shown by dotted lines in Fig. 40, and when said keys U^{17} are inserted into the key-holes U^{18} of said operating rods U^{15} , then said supporting head M^{50} with said axle E and piercer or center E^9 will all be longitudinally moved or operated together by the pressure in the cylinder O acting upon the piston and its rods O^1 , O^2 , which rods are operatively connected with said supporting head M^{50} (see Fig. 40) and are longitudinally moved or operated, as and in the manner set forth in before described matter with reference to Figs. 6 to 11 inclusive, and as hereinafter shown and described with reference to other figures, and also as shown and described in my said original application.

When said piston-rod U^2 is connected with said cross-head U^{20} and said keys U^{17} are removed from the key-holes U^{18} of the operating rods U^{15} , as shown in Figs. 30, 31 and 40, the operation may be as follows: With said power or pressure means operatively connected with the supporting head M^{50} , said supporting head with its forming-die, for instance W^{23} , is moved into the position for instance shown in the Figs. 1 and 5 and hereinbefore described and, in that position said parts M^{50} and W^{23} may be retained during the operating process, while said axle E and piercer or center, for instance E^9 , are longitudinally moved or operated by said power or pressure means operatively connected with said cross-head U^{20} in the following manner:—The cross-head U^{20} is thereby moved from the position

shown in Fig. 30 to the position shown in Fig. 31, as indicated by the distance x^7 , and during this movement, said part M^{51} is moved by said cross-head U^{20} and operating rods U^{15} from the position shown in Fig. 30 to the position shown in Fig. 31, as indicated by the distance x^7 between the end-plate U^{31} and said part M^{51} , and, the axle E with its piercer or center, for instance E^9 , parts M^7 , M^8 , M^{51} , U^{14} , U^{20} , e^{18} , U^{22} , U^{26} , U^{25} , U^{15} and U^{27} are moved from their positions shown in Fig. 30 to the positions shown in Fig. 31, as indicated by the distance x^7 between the position of said piercer or center E^9 in Fig. 30 and the position of said piercer or center E^9 in Fig. 31.

Said end plate U^{31} is firmly bolted to the outer end M^{52} of the upper portion of said supporting head M^{50} , by the screws M^2 , as shown. From the ends of their outer threads, these screws M^2 have reduced extensions U^{16} , to the outer ends of which extensions is fastened a head or guide plate U^{28} , as shown. This guide plate is provided with bearings for said operating rods U^{15} , U^{15} , U^{15} , U^{15} and the end portion U^{27} of the cooling medium inlet piece U^{25} , as shown. Said guide plate U^{28} is rigidly fastened to the supporting head M^{50} by the means shown and, when operating said axle E with its piercer or center, for instance E^9 , independently of said supporting head M^{50} , said parts U^{15} , U^{15} , U^{15} , U^{15} and U^{27} will slide in the bearings of said guide-plate U^{28} .

With reference to Figs. 30, 31, 32, 39 and 40; said axle E is provided with a sleeve U^{20} at or near the flange e^{18} , which sleeve is formed and rotatably fitted to the axle E as shown. Said sleeve is fitted at both ends with a stuffing box portion, as shown, and at its middle portion is provided with an annular internal recess U^{21} , as shown. The stuffing box portion at one end of said sleeve fits over the axle, as shown, and between the shoulder of said axle and the shoulder formed by the end portion of said recess U^{21} packing is placed to prevent leakage at this end. The other end of said sleeve receives a packing box and gland U^{22} which is fastened to the adjacent end of the axle E by screws as shown. A hollow piece is provided which consists of the small cylindrical portion U^{24} and the large cylindrical portion U^{23} . The open end of the large portion U^{23} is rigidly attached to the pipe e^{11} , as shown, and the shoulder formed by said small and large cylindrical portions is in contact with the inner end face of said gland U^{22} . The small cylindrical portion U^{24} passes through said gland U^{22} and into the threaded female end portion U^{26} of the cooling medium inlet piece or elbow, consisting of the sliding and supporting portion U^{27} , the elbow portion U^{25} and said end portion U^{26} , as shown. Said pipe e^{11} with

its said parts U^{23} , U^{24} , U^{26} , U^{25} , pipe for the cooling medium inlet e^{14} and sliding supporting portion U^{27} do not rotate with said axle E , rotation of these parts being prevented by one of the rods U^{16} and a stop-rod U^{28} which are rigidly attached to said parts U^{21} and U^{28} and are in contact with opposite sides of said pipe for said inlet e^{14} (see Fig. 32). All other parts of said axle E are rotating therewith with exception of said sleeve U^{29} , which is prevented from rotating by one of said rods U^{16} and the stop-rod U^{22} which are rigidly attached to said parts U^{21} and U^{28} and are in contact with the outlet pipe e^{18} (see Fig. 32).

The cooling water or other cooling medium enters at arrow e^{14} , passes into and through said elbow-portion U^{26} and pipe e^{11} and then flows in the direction indicated by the arrows e^{15} , around the outside of said pipe e^{11} and through the openings e^{17} into the recess U^{21} of said sleeve U^{29} , and from there through the short pipe e^{18} (see Figs. 30 and 31) and into and out through port e^{19} and channel e^{20} (see Figs. 39 and 40) and from there through channels formed in parts of the bed-plate, for instance B^2 , from which it is taken away by any suitable means, such as pipes or channels, &c. By the means shown in Figs. 30, 31, 32, 39 and 40, said supporting axle E with its piercer or center, for instance E^0 , the journals M^1 , M^4 and M^5 , and the ball thrust bearing formed by the parts M^1 , M^4 and M^5 are practically kept cool. By this means part of the heat is also taken away from the central or supporting portion of a heated work-piece to give to the supporting surface or the portion of the work-piece adjacent said piercers or centers a greater or harder supporting resistance. The inward flow of the cooling medium indicated by said arrow e^{14} can easily be regulated by a valve.

The cooling water or other cooling medium for the outer sides of said supporting head M^{50} enters, as indicated by the arrow M^0 (see Figs. 39, 40 and 106), into a water or other cooling medium reservoir or box M^{11} (more fully shown and described in my said original application) which is formed in the upper part of said head M^{50} and which box has openings M^{11} at its lower end extending the total width of said box at opposite sides of said head M^{50} . Through these openings the cooling water or other cooling medium flows down the sides of said supporting head M^{50} , as for instance indicated by the arrows M^{18} (see Figs. 40 and 106) and into and through said port e^{19} and channel e^{20} (see Figs. 39, 40 and 106) from where it flows through the before-mentioned channels formed for instance by parts of the bed-plate B^2 , from which it is taken away by any suitable means, such as pipes, channels, &c. By the means described, the supporting

head M^{50} may practically be kept cool and thus assist in keeping said axle E and its journals cool and also assist in taking part of the aforesaid heat away from the supporting surface of the work-piece to give said supporting surface in contact with said piercers or centers a greater or harder supporting resistance. The flow of water or other cooling medium over the opposite sides of said head M^{50} can easily be regulated by a valve.

The cooling arrangement provided for the other supporting head M may be either similar to the one above described for supporting head M^{50} , or as shown and described in my said original application, or any other arrangement may be provided which will produce the same effect.

Figs. 42 and 43 show the forming-die, for instance W^1 , supported by the edging and die-supporting roll, for instance J^{50} , and by the die-supporting roll, for instance G^{14} , and in position ready to receive a work-piece. In the position shown, the roll G^{14} with its die-supporting portion g^{130} is supporting the forming-die in both radial and lateral directions, and with its edging or supporting portion g^{137} is against or in contact with the face finishing roll H as shown. The supporting portion g^{137} of said roll G^{14} also serves as an edging roll portion, as for instance shown by the roll G^{61} , Fig. 48. Said roll may also be constructed so that part thereof serves as an edging roll portion, such as for instance shown by the roll G^{111} in Fig. 101, or said roll or a part or parts thereof may serve other purposes, as hereinafter shown and described. The face rolls H and K may be moved at right angles to the axis of a supported work-piece during the operating process, as may be desired, or they may be retained at any desired radial distance or distances from the axis of the supported work-piece, such as the case may require, or both face rolls H and K may be moved together or in unison, as hereinbefore described and as more fully described in my said original application. In the positions shown in Figs. 42 and 43, said roll J^{50} with its die-supporting portion j^{40} is supporting the forming-die in both radial and lateral directions, and with its edging roll portion j^{29} is against or in contact with the face rolling roll K , as shown. Said edging and die-supporting roll may also be formed entirely different and may also be formed to serve other purposes than the one shown in Fig. 43, all as hereinafter shown and described. In these Figs. 42 and 43, during the operating process against a work-piece, said face roll K will operate upon the peripheral face of the work-piece continually and as the work-piece increases in diameter, said face roll may be moved a certain distance indi-

cated, for instance, by x^6 away from the edge of forming-die W^1 until the desired diameter of the work-piece has been reached, when said movement of said face roll K will be automatically stopped and retained, and during said movement of said face roll K away from the edge of forming-die W^1 the edging roll part j^{29} of said roll J^{50} will operate against or in contact with the side 10 or edge of the marginal or rim portion of the work-piece as for instance shown by roll J^{61} in Fig. 66. In the Figs. 42 and 43 the edging roll part j^{29} of roll J^{50} may be driven by its shaft J while the die-supporting portion j^{40} of said roll J^{50} may be 15 rotatably fixed and permitted to turn loose for instance on a journal provided on said shaft J ; such loose roll portions are shown and described in my said original application for said edging and web rolling rolls.

In Fig. 43 the supporting head M^{50} together with its axle E and piercer or center, for instance E^6 , is moved for instance the distance x^7 , as indicated by dotted lines.

25 In Fig. 50 the supporting head M^{50} is retained in fixed position while the axle E with its piercer or center, for instance E^6 , is moved for instance the distance x^7 , as indicated by dotted lines and as above described.

30 In Fig. 43 the forming-die W^1 is formed at the peripheral portion of its operating or forming side with the inclined peripheral face w^8 which is adapted to form the inner peripheral face of the marginal or rim portion of the side of the work-piece next to the forming-die to the inclined form f^{18} , in for instance Fig. 85. Said face w^8 is the same as and for the purpose hereinafter described with reference to the Figs. 113, 40 114, 116 and 117.

In Fig. 44 the forming-die W^{10} is formed at the peripheral portion of its said forming side with the peripheral face w^8 which is adapted to form the inner peripheral face 45 of the marginal or rim portion of the side of the work-piece next to the forming-die to the form f^{20} , in for instance Fig. 85 or 87.

In Fig. 45 the die-supporting portion of the rolls J^{60} and G^{61} are formed with stepped 50 portions, each having its peripheral face formed straight, or approximately so, thereby forming shoulders which radially support the forming-die W^{11} in opposite directions as shown.

55 In Fig. 46 is shown, at F^2 , a rolled or formed and dished disk-wheel or center, such as used for instance in some tired car wheels; the process for rolling and dishing the same being similar to the process illustrated in Figs. 17 and 18 for rolling and dishing the car wheel therein shown; that is, the rolling and forming is performed 60 with the use of only the forming-die W^{12} , rolls J^1 , J^{61} , and K having peripheral rolling face K^8 formed as shown, and with

the supporting heads M , M^{50} and axles E , E with their respective piercers or centers, for instance E^6 , E^6 as shown, and the rim portion is similarly rolled or formed as per illustration Fig. 117, and as hereinafter 70 more fully described.

In Fig. 47 is shown at F^2 a dished car wheel rolled or formed and dished with only the use of the operating parts shown, and as hereinafter more fully described; 75 the process for rolling and dishing being similar to the process illustrated in Figs. 19 and 20 for rolling and dishing the car wheel therein shown, and the rim portion is similarly rolled or formed as per illustrations Figs. 115 and 116, and hereinafter 80 fully described.

In Fig. 48 is shown at F^2 a dished car wheel rolled or formed and dished with only the use of the forming-die W^{13} , rolls 85 G^{55} , G^{61} formed as shown, face roll H having its peripheral rolling face H^4 formed as shown, and face roll K having its peripheral rolling face or operating portion K^{28} formed as shown, and with the supporting 90 heads, axles and piercers or centers as shown. It is to be noted that in this figure the edging roll portions g^{137} , g^{127} of both rolls G^{55} and G^{61} are operating upon the opposite sides 95 or edges of the rim portion of the wheel F^2 as shown, the face roll K is formed and is acting as a finishing roll, and the rim portion is similarly rolled or formed as per illustrations Figs. 115 and 116, with the exception that both the inner peripheral faces of 100 the rim are formed as at f^{20} in Fig. 87 or 114.

In Fig. 49 is shown at F^2 a dished car wheel rolled or formed and dished with the use of the rolls and other operating parts as shown. The process for rolling and dishing 105 is similar to the process illustrated in Figs. 23 and 24 for rolling and dishing the car wheel therein shown and as hereinafter described in rolling examples with reference to other figures. In this Fig. 49 the inner 110 peripheral faces and outer peripheral face of the rim portion of the work-piece or wheel are acted upon by the web rolling roll G^1 , forming-die W^{13} , and face finishing roll H ; while the edging roll part j^{29} of the roll 115 J^{61} and the roll J^6 are acting upon the opposite sides of the rim, as shown, and finishing the same to its desired width.

In Fig. 101, the forming-die, for instance W^{21} , is positively driven from the shaft J 120 by bevel gear j^{40} meshing with the teeth w^8 of a bevel gear provided on said forming-die W^{21} . The work-piece and the other rolls are not shown in this figure. The said piercers or centers, for instance E^{15} and E^{16} 125 are similar to the ones shown for instance in Fig. 55, 58 or 62. Said forming-die W^{21} is mainly supported laterally by the portion g^{140} of the roll G^{111} and by the portion j^{48} of the roll J^{78} and is mainly supported 130

dially in opposite directions by the shoulder g^{142} of the roll G^{111} and by the shoulders j^{42} and j^{42} of the roll J^{68} , as shown. The parts shown in Fig. 101 are brought and retained in the position shown and are ready to receive a work-piece and, when receiving the work-piece, said piercer or center E^{16} with its supporting head M is pulled back into the position for instance indicated in the Figs. 1, 5, 8, 12, 16, or indicated by the dotted lines for the piercer or center E^{16} in Fig. 55. In this Fig. 101, the face finishing roll H is retained during the operating process at a radial distance from the axes of said piercers or centers, for instance E^{16} , E^{16} , which distance equals the radius of the diameter of the finished wheel or other finished object. It is to be observed that the shoulder g^{142} of the portion g^{144} of the roll G^{111} bears against or in contact with said forming-die W^{21} and that the other shoulder g^{143} of said portion g^{144} bears against or in contact with the end collar or flange h^1 of the face roll H , as shown; thereby forming a continuous rolling surface extending outward from the periphery of said forming-die W^{21} and adapted to act against one side of the marginal or rim portion while said roll H acts against the total peripheral face of the work-piece or wheel including the rounding of the outer corners of the tread and flange of the wheel. The beaking or roughing roll K in this figure, is adapted to commence operating against the peripheral face of the work-piece from its position against said forming-die W^{21} , as shown, and during the operating process against the work-piece, said roll K will operate upon the peripheral face of the work-piece continually and as the work-piece increases in diameter, said face roll K moves with the enlargement of said diameter. In this figure the center for instance E^{16} is firmly attached to axle E by the shoulder e^2 formed on said axle and by the pins e^1 , as shown, or by any other suitable means. Feathers e^{48} , e^{46} are provided on said center E^{16} and the bore of said forming-die W^{21} is provided with key-ways fitting slidably over said feathers, thus causing said piercer or center E^{16} with its axle E to be rotated by said forming-die W^{21} , as shown in the Figs. 101 and 102.

In Fig. 103 said forming-die, for instance W^{22} , is also positively driven by the means as shown, which are similar to the means shown in Fig. 101. In this figure, a forming-die W^{22} is shown, of which the forming-portion or forming side is similar to the forming-die shown in Fig. 58. With such a forming-die, as for instance shown in Figs. 58 and 103, the diameter of the work-piece will be enlarged during the forming process and the metal at the peripheral face of the work-piece will not be rolled nor

worked during the forming process; thereby the metal in the peripheral face and rim portion will be extended instead of being compressed, which extension will produce incipient cracks in the tread and flange of the finished product. However, for light service, wheels may be formed in such dies. The parts shown in Fig. 103 are in position ready to receive a work-piece and when receiving the work-piece, said piercer or center E^{16} is pulled back into the position for instance indicated in the Figs. 1, 5, 8, 12, 16, or indicated by the dotted lines for the piercer or center E^{16} in Fig. 55. In this Fig. 103, said forming-die W^{22} is provided at its outer or peripheral portion with a straight peripheral face and with a circumferential track or groove w^6 , and the herein named face rolls H and K at their peripheral portion are each formed as shown; that is, the peripheral portion of the roll K is formed with the portion k^{39} and the straight peripheral faced or cylindrical portions as shown, and the peripheral portion of the roll H is formed with the portion H^{61} and the straight peripheral faced or cylindrical portions as shown, and both said portions k^{39} and H^{61} are correspondingly shaped, as shown, to fit said track or groove w^6 , and thereby mainly support or retain said forming-die W^{22} laterally or axially against or in contact with the die-supporting portions j^{50} , j^{42} and j^{42} of the roll J^{68} and with the die-supporting portions g^{140} and g^{141} of the roll G^{112} , and mainly support said forming-die W^{22} radially in opposite directions, as can be observed from the Fig. 103. The said piercer or center, for instance E^{16} , is firmly attached to its axle E by the shoulder e^2 formed on said axle and by the pins e^1 , as shown, or by any other suitable means. Feathers e^{48} , e^{46} are provided on piercer or center E^{16} , and the bore of said forming-die W^{22} is provided with key-ways fitting slidably over said feathers, thus causing said piercer or center E^{16} with its axle E to be rotated by said forming-die W^{22} , as shown in Figs. 103 and 104.

Figs. 105 to 107 inclusive, illustrate the arrangement or device shown in Fig. 5 in detail on an enlarged scale, for supporting the forming-die, for instance W^{22} , on loose rolls X^3 , X^4 which are fixedly and rotatably attached to the supporting head M^{60} and carried thereby.

In using this device, the rolls shown in Fig. 1; that is, for instance G^{14} and J^{69} , together with their shafts and other operating parts for these rolls G^{14} and J^{69} are removed and in place thereof is substituted said arrangement or devices as shown in Fig. 5. In this arrangement the whole work-supporting head M^{60} together with said rolls, for instance X^3 , X^4 , the forming-die, for instance W^{22} , and the piercer

or center, for instance E^9 , may be moved forward or backward and adjusted to their proper positions, as for instance shown in Fig. 5, by the pressure in its pressure cylinder O (see for instance Figs. 6 and 40), the piston of which is operatively connected with said work-supporting head M^{50} and may be adjusted so that the edging roll part g^{187} of said die-supporting roll X^3 is 5 in contact with said face roll H and the edging roll part j^{29} of said edging and die-supporting roll X^4 is in contact with said face roll K , as shown. At the commencement of the rolling operation, said face roll 10 K is moved toward and against or in contact with the forming-die W^{23} , as shown in Figs. 5 and 105, and said face roll H is moved a proper radial distance from the axis of said piercers or centers, for instance 15 E^8 , E^9 . In some cases, said face rolls K and H may be moved toward or against and away from the peripheral face of the work-piece in unison; that is, each face roll will be moved the same distance, or said 20 face rolls K and H may both be moved into a position which is a certain radial distance or distances from the axis of said piercers or centers E^8 , E^9 and be retained in said radial position until the work-piece 25 or wheel is finished, as hereinafter more fully described.

In the illustrations shown in Figs. 40 and 41, said supporting head M^{50} with its axle E , piercer or center, for instance E^9 , 30 forming-die, for instance W^{23} , and supporting rollers for instance X^2 , X^2 may be moved into the position for instance shown in Fig. 5, and therein said head M^{50} and forming-die W^{23} may be retained in a fixed 35 position; and when for instance dishing the work-piece or wheel said piercer or center, for instance E^9 , with its axle E is moved axially without moving said head M^{50} , as and in the manner hereinbefore described 40 with reference to the Figs. 30 to 41 and Figs. 105 to 107, and also with reference to other figures.

In Fig. 105, in which said device is shown in sectional plan view, outer brackets X^{10} , X^{11} are firmly fastened to supporting head M^{50} by screws X^{18} , and inner plates or brackets X^8 , X^9 are firmly fastened to the supporting head M^{50} by bolts and screws X^{21} and X^{22} , as for instance shown. Journal pins or spindles X^5 , X^6 are provided, of which one is firmly attached to the brackets X^8 and X^{10} located at one side of the supporting head M^{50} . The inner or screw end of said axle X^6 is screwed into threaded hole X^7 of the bracket X^8 and the outer portion of said axle X^6 is provided with the parts X^{14} and X^{15} formed as shown (see also Figs. 108 and 109) of which the part X^{14} is fitted into the hole X^{12} of 55 bracket X^{10} . A key X^{17} prevents said spin-

dle from turning or from becoming loose. The edging and die-supporting roll X^3 is fitted with bearings X^6 , X^6 on which said roll X^3 is rotatably supported by said spindle X^5 and is held against endwise movement by said brackets X^8 , X^{10} as shown. Said other edging and die-supporting roll X^4 is rotatably supported by said other spindle X^6 and is held against endwise movement by said other brackets X^9 , X^{11} in a similar manner as described for the roll X^3 . Said forming-die, for instance W^{23} , is laterally or axially supported by the die-supporting parts of said rolls X^3 and X^4 and by the rollers X^2 , X^2 (see also Figs. 106 and 107) and is radially supported in opposite directions by the shoulders formed by the stepped portions of said rolls X^3 , X^4 , as shown in Figs. 105, 106 and 107.

The cooling water or other cooling medium for the outer sides of said supporting head M^{50} , as hereinbefore described with reference to Figs. 39, 40 and 106, enters, as indicated by the arrow M^9 , into a cooling medium reservoir or box M^{11} and out of openings M^{17} at the lower end of said box, down the sides of said supporting head M^{50} , as for instance indicated by the arrows M^{18} (see also Fig. 40), and into and through said port e^{19} and channel e^{20} , as before described with reference to said Figs. 39 and 40.

The supporting head M^{50} shown in Figs. 105, 106 and 107 is provided at the outer end M^{52} of its upper portion with the end plate U^{31} and the parts connected therewith, as for instance shown and described with reference to the Figs. 30, 31 and 40, and the operations of this head M^{50} and the operation of the axle E and piercer or center of this head M^{50} ; that is, the manner for moving or operating the supporting axle E together with its piercer or center, for instance E^9 , independent of its supporting head M^{50} , or for moving said supporting head M^{50} together with said axle E and piercer or center, for instance E^9 , is the same as hereinbefore described with reference for instance to Figs. 1, 5, and 30 to 41 inclusive.

From the above it will be seen that, with the herein named edging and web rolling roll and the forming-die formed as herein shown and with the inner rolling or operating portion of the web reducing roll part j^{28} of said edging and web rolling roll, for instance J^1 , J^7 or J^{58} , &c., formed sufficiently conical in one direction, and with the peripheral forming portion or peripheral forming face of the forming-die adapted to form the inner peripheral face of the marginal or rim portion of the work-piece or wheel at its one side formed sufficiently conical in the other direction, as and for the purpose hereinafter fully described with reference for instance 115 120 125 130

to the Figs. 113, 114, 116 and 117, and efficient rolling or forming action is obtained, which during the formation of the web part toward the rim part, causes the metal to flow in the proper directions; that is to say, toward the rim part, within the latter, and peripheral thereto. The lateral flow of metal is limited by the roll parts j^{29} , j^{29} of the edging and web rolling roll and the 5 edging and die-supporting roll, and when this lateral flow of the metal is thus arrested, the continued flow thereof will be peripheral to the rim. It will be observed that the radial flow of the metal is limited 10 by the rolling surface of the tread or face rolling roll K, and when the radial flow is thus arrested, the continued flow of the metal will be peripheral to the rim, as for instance partly illustrated in Figs. 53, 20 66, 113, 116 and 117. From this and from the matter described below with reference to Figs. 53, 66, 113, 116 and 117, and with reference to other figures herein shown, it is to be observed that the metal, when being 25 rolled or formed from the blank or other work-piece into a wheel or other article, is, especially in the tread and flange or rim portion, not expanded radially, and therefore does not produce incipient cracks in 30 the tread and flange portions of the rim, but is truly rolled or formed and increases in density with increased working, thus giving to the metal both its due maximum strength and maximum resistance to wear. In other 35 words, this method of rolling or forming produces the same effect in the metal of the rim portion as if the web portion of the wheel were not in existence and the rim portion rolled or formed its total width 40 on its inner peripheral surface or surfaces as is done on its outer peripheral surface consisting of the tread and flange. In Fig. 66, for instance, is shown such edging and web rolling roll, for instance J^{69} , rolling or 45 forming the web and rim parts of the work-piece F^1 central with the hub part, as shown and therein with the inner rolling or operating portion of the web reducing roll part j^{28} of the edging and web rolling roll J^{69} 50 formed sufficiently conical and with the peripheral forming face w^3 of the forming-die W^{12} also formed sufficiently conical as for instance shown and as and for the purpose hereinafter more fully described, the 55 centers of the pressures caused by the so conically formed inner rolling or operating portion of said web reducing roll part j^{28} of said roll J^{69} and by the so conically formed peripheral face w^3 of said forming-die W^{12} , are illustrated in the Figs. 113, 116 and 117 as acting at the centers of the 60 lengths of said conically formed inner rolling or operating portions and at right angles thereto against the work-piece, as is indicated by the arrows p and p^1 of said 65 pressures, and the resultant pressure r from said pressures p and p^1 is therein indicated in the direction shown by the arrow for said resultant pressure r , and the actual flow of the metal will be in a lateral, radial and 70 peripheral direction, that is, toward the roll J^{69} in Fig. 66 and toward the portion w^3 of the forming-die W^{12} and toward the edging roll portion j^{28} of the roll J^{69} (see Fig. 66) and peripheral to the rim and in a radial 75 and peripheral direction; that is, toward the periphery of the work-piece in the direction of the arrow r (see Fig. 113, 116 or 117) and against the face rolling roll K and from there the metal will flow peripheral to 80 the rim, and said lateral flow of metal is limited by said edging roll parts j^{28} , j^{28} of said rolls J^{69} and J^{61} (see Fig. 66) from where the metal will flow peripheral to the rim, and the said radial flow of metal is 85 limited by the rolling surface of the said tread or face rolling roll K, from where the metal will flow peripheral to the rim. 90

Figs. 110 to 114 inclusive are sections of the rim portion of car wheels illustrating diagrammatically the flow of metal caused by various forms of rolls or other operating parts, and therein the pressures caused by the rolls or by the roll and forming-die against the surface of the metal in contact 95 with the rolls or in contact with the roll and forming-die are assumed to be uniformly distributed at said surface, as indicated by the arrows pointing against said surfaces and the direction of the flow of metal from 100 said arrows toward the inner region of the rim portion is indicated by the pressure lines of said arrows. The flow of metal illustrated by pressure lines parallel to each other indicate a uniform compression of 105 metal. The flow of metal illustrated by diverging pressure lines indicate that said uniformly distributed pressures at said surfaces in contact with the rolls or other operating parts are becoming less toward 110 the inner region and peripheral face of the rim portion, and therefore the metal in those portions of the rim having said diverging lines is not condensed to the same degree as is the metal in the portions having 115 parallel pressure lines and which degree of condensing becomes less and less as the distances between said diverging lines become greater; and if the rim is not rolled at its outer peripheral face simultaneously with 120 the rolling or forming of its inner peripheral faces, the metal will be extended instead of being compressed and thereby produce incipient cracks in the tread or outer peripheral face of the rim. The finished peripheral face of the car wheel is indicated by f^{12} and the outline of each of said sections is shown in heavy lines. In the Figs. 110, 111 and 112 the center line of the rim and adjacent web portion is indicated by y , and 125 130

said inner face or faces of the rim portion in contact with the rolls or other operating parts are indicated by f^{18} . In Fig. 110, the portions of the rim in which the metal is not properly condensed is indicated by the distances d^1, d^2 occupied by said diverging lines. In Fig. 111, the portions of the rim in which the metal is not properly condensed is indicated by the distances d^3, d^4 occupied by said diverging lines. The rolling or forming of the rim portion as and in the manner described with reference to Figs. 110 and 111 does not properly work the metal in the rim and therefore forms a rim which during the rolling process, has already been weakened where its strength is needed and of which the tread will wear out quickly and shorten the life of such wheel, all of which may be observed on present wheels in actual use. In Fig. 112 is illustrated a section of a tire having for instance no web, such as used for some tired car wheels. From this figure it can easily be observed that the metal in such objects having a straight inner face without a web as shown, can be rolled to practically uniform density, as indicated by the parallel pressure lines for the total pressure P , and the metal in the rim portion of car wheels and similar objects having each a web formed integral with the rim, can be rolled or formed in accordance with my invention to practically uniform and maximum density, as can be done with rims having no web portion.

Therefore and in order to produce said effects or results in the metal of the rim portion of the work-piece or car wheel as hereinbefore referred to with reference to Figs. 113, 114, 116 and 117, and to entirely avoid the improper working of the metal described with reference to Figs. 110 and 111, I form the inner rolling or operating portion of the web reducing part j^{28} of said edging and web rolling roll for instance J^1 and the portion w^3 of the forming-die, for instance W^1 (see Fig. 113, 116 or 117), sufficiently conical, so that, during the operating process against the work-piece, the face of said conically formed portion of j^{28} of said roll J^1 is sufficiently inclined from its lateral apex toward the inner end of the roll J^1 and the portion w^3 of said forming-die W^1 is sufficiently inclined from its lateral apex toward the inner end of the roll J^{59} ; that is to say, that when for instance, the web reducing part j^{28} of said roll J^1 and the forming side of the forming-die W^1 are against the finished web, then said face of said conically formed portion of each of said parts j^{28} and w^3 is sufficiently inclined from the side of the web outwardly in the direction away from the axis of the work-piece, as for instance in Figs. 53, 66, 113, 116 and 117. Said in-

clination of each of said parts j^{28} and w^3 I therefore form sufficiently large enough so as to roll or form the inner peripheral faces of the rim portion sufficiently inclined outwardly toward the peripheral face of the work-piece so that during the rolling or forming of the rim portion, for instance to the rudimentary form shown in the Figs. 53, 66 and 113, the metal is caused to flow in the proper directions to assure compression of the metal in said rim portion to uniform or to practically uniform density, as is distinctly shown and diagrammatically illustrated in Fig. 113, 116 or 117. In Figs. 113 and 114 is diagrammatically illustrated and distinctly shown the result of the rolling or forming of the rim of a car wheel in accordance with my invention hereinbefore and hereinafter described with reference to other figures.

Fig. 113 distinctly shows what is meant by the herein used words "sufficiently conical" or "sufficiently inclined" and therein is shown said rim portion rolled or formed for instance to the rudimentary form shown for instance in the Figs. 53, 66 and 93 and other figures; and in Fig. 113 is also shown in dotted lines said rim portion rolled to finished form, and the center pressures p, p^1 are the same as before described with reference to Fig. 113, 116 or 117; the pressure lines for each of said pressures p, p^1 being parallel to each other in the directions of the arrows and at right angles to said inclined faces of said parts j^{28} and w^3 . The said pressures p, p^1 from said sufficiently inclined face of said roll part j^{28} and from said sufficiently inclined face w^3 of the forming-die W^1 thus applied during the rolling or forming of said inner rim portion have 100 rolled or formed said inner faces f^{18}, f^{18} of the so rudimentarily formed rim portion sufficiently inclined, as distinctly shown by the pressure lines for each of said pressures p, p^1 which caused the metal during said 105 rolling or forming of the rim portion to flow in the proper directions to be compressed to uniform density, as distinctly illustrated by said parallel pressure lines for each of said pressures p, p^1 , while at the same time the pressures p^5, p^6 against the lateral sides of the rim from the edging roll parts j^{28}, j^{29} of said rolls J^1 and J^{59} have caused the metal to flow into the inner region of the rim in the direction of the arrows of the pressure lines for said pressures p^5, p^6 and have rolled the rim to desired lateral thickness and while at the same time the pressure p^7 against the peripheral face of the rim portion from the face beaking 110 or face roughing roll K having its rolling face K' formed as shown, has caused the metal to flow also into the inner region of the rim in the directions of the arrows of the pressure lines for said pressure p^7 and has 115 120 125 130

rolled said peripheral face to the beaked or rudimentary form K' as shown, thereby having rolled or formed said metal in the rim and adjacent web portion simultaneously on all its surfaces by rolls, with the exception of the one inner peripheral face of the rim formed with the inclined face w^3 of the forming-die W^1 by the action of rolls; all such rolls being situated in a plane passing laterally through said rim and adjacent web portion and having compressed said metal simultaneously on all its surfaces to uniform and maximum density, or practically so, while at the same time the rim portion has been rolled to said rudimentary form, shown for instance in the Figs. 53, 66 and 113 and other figures. The so rudimentarily formed rim is then rolled or formed with rolls situated at another point of the rim portion to finished form whereby its metal is still further condensed, as diagrammatically illustrated in the Fig. 114. In Fig. 114, said so rudimentarily formed rim portion, rolled or formed in accordance with my invention, is shown in dotted lines, and the finished rim and adjacent web portion shown rolled or formed in accordance with my invention during the finishing rolling process to finished form; is shown in heavy lines, and during the finishing rolling process with the rolls G^1 and H operating against the rim portion at another point thereof, with the aid of the forming-die W^1 the web finishing roll G^1 with its web finishing roll part g^{18} rolls the inclined face f^{18} at one side of the work-piece to the finished form f^{20} , while the inclined face f^{18} at the other side of the work-piece maintains its form f^{18} . Simultaneously therewith, the peripheral face finishing roll H is rolling said beaked or rudimentarily formed peripheral face K' to the finished form f^{12} and the edging roll parts j^{20} , j^{20} of said rolls j^1 and j^{20} (of which rolls the roll j^1 has now been moved somewhat toward the axis of the work-piece, as for instance indicated by the distance f^{24} in said Figs. 113 and 114) are still operating in contact with the sides f^{22} , f^{22} of the rim at another point thereof and are limiting the lateral flow of metal and maintaining the lateral thickness in the rim to which the same has been rolled during the rolling described with reference to Fig. 113; the combined action of said forming-die W^1 and said rolls J^1 , J^{20} , G^1 , and the die-supporting roll, for instance G^{14} , and the face finishing roll H during said finishing rolling process, roll or form the rim and adjacent web portion to the finished form shown in Fig. 114. Said Figs. 113 and 114 distinctly show and diagrammatically illustrate that the metal in the whole rim portion, rolled or formed in accordance with my invention, is rolled or worked to uniform and maximum den-

sity, or practically so, especially in the tread, flange and root of the flange where the strength and resistance to wear is mostly needed. It is, of course, to be understood that in order to produce said results, the rim portion must be rolled or formed first, for instance, to rudimentary form, as and in the manner described with reference to Fig. 113, before the same is rolled to the finished form shown in the Fig. 114, and that the rolling of the said inclined face f^{18} and the rolling of said beaked peripheral face K' to their finished forms during the finishing rolling process will not disturb the density of the metal to which it has been compressed during the process described with reference to Fig. 113, but will still more compress the metal, especially so in the tread, flange and root of the flange where the strength and resistance to wear is mostly needed, as can easily be seen from said Fig. 113.

From the foregoing it will now be observed that, in rolling or forming for instance car wheels with the edging and web rolling roll and the edging and die-supporting roll formed as herein shown and as and for the purpose described with reference to Figs. 113 and 114, and with the lateral thickness or width of said tread or face rolling roll K being the same as the lateral thickness or width which the rim portion of the car wheel is to have when finished, as is for instance shown in the Figs. 6, 7, 17, 19, 46, 47, 53, 56, 63, 66, 81, 100 91, 95 and 97, and diagrammatically illustrated in Figs. 113, 116, and 117, thereby, and with said roll K formed as shown and as and for the purpose herein described and diagrammatically illustrated in Figs. 113 105 and 114, and with the said edging and web rolling roll and said edging and die-supporting roll formed as for instance herein shown and as and for the purpose above described with reference to the Figs. 113 110 and 114, and with all said edging and web rolling roll and said edging and die-supporting roll and said face roll K and the operating portion w^3 of the forming-die situated in a plane passing laterally through 115 the work-piece at one side of its axis, the metal in the peripheral face and the whole rim portion of the work-piece or car wheel is worked continually, during the rolling or forming of the rim to rudimentary form, 120 upon all its surfaces simultaneously with said operating portion w^3 of the forming-die and said three rolls so formed and so situated as before said and as shown for instance in said Figs. 55, 66, 113 and other 125 figures, and in then rolling the so rudimentarily formed rim to finished form, as and for the purpose for instance described with reference to Figs. 113 and 114 and, which to my knowledge together with the result 130

obtained thereby, as for instance above described with reference to the Figs. 113 and 114 was never done or accomplished before in rolling or forming car wheels, whereby 5 the metal in said peripheral face and in the whole rim portion is uniformly condensed to its maximum, or practically so, thereby giving the metal in said peripheral face and in the whole rim portion its due 10 maximum and uniform strength and its due maximum and uniform resistance to wear; and, as any surplus of metal in the work-piece can be worked during the rolling or forming process, for instance, into the 15 inner rim and adjacent web portion, the said peripheral face and the whole rim portion of the car wheel can also be rolled or formed, by my process, smooth on all its surfaces to the desired form without leaving a raised circular portion or fin, which 20 would have to be removed afterward by turning or other costly means.

Figs. 115, 116 and 117 are similar diagrammatic illustrations as Figs. 113 and 25 114. Figs. 115 and 116 relate, for instance, to the rim of a car wheel rolled or formed in accordance with my invention with only the use of the forming-die and the four rolls as described with reference for instance to 30 Figs. 19, 20 and 47; that is, (with reference to Figs. 115 and 116) the rim is rolled or formed with the forming-die, for instance W¹, the herein named edging and web rolling roll, for instance J¹, the herein named 35 edging and die-supporting roll, for instance J⁶¹, the face rolling roll K having its rolling face K¹ formed as shown, and the face finishing roll H. With such an arrangement, the rim portion is rolled or formed direct 40 to finished form, with the exception that the outer corners of the tread and flange are rounded to proper form or shape with the finishing roll H situated at another point of the rim. Fig. 117 relates, for instance, 45 to the rim portion of a disk-wheel or center such as used for some tired car wheels having a rim portion similar to the one shown at F² in Fig. 46 or 96, and rolled or formed in accordance with my invention, with only 50 the use of the forming-die and the three rolls as, for instance, described with reference to Figs. 17, 18 and 46; that is, (with reference to Fig. 117) the rim portion is rolled or formed with the forming-die, for 55 instance W¹, the herein named edging and web rolling roll, for instance J¹, the herein named edging and die-supporting roll, for instance J⁶¹, and the face rolling roll K having its rolling face K¹ formed as shown. 60 With the arrangement shown in Fig. 117, the rim portion is rolled or formed direct to finished form, as shown. The pressure lines in said Figs. 116 and 117 and the result derived are similar to the ones described with reference to Fig. 113.

A car wheel or other circular article may also be rolled or formed as for instance described in the following with reference to Figs. 51 to 54 inclusive, in which I have, for instance, illustrated in brief, a rolling or 70 forming process or steps according to my invention, such as I prefer to employ for completely rolling or forming and dishing the car wheel shown at F² in Fig. 54, from a blank or work-piece such as shown at F in Fig. 51 having, for instance, a conical central hole, as shown. In these figures the forming-die W⁶ is formed at its one side with a long central hub portion, as shown. The axle E of the supporting head M⁵⁰ is 80 provided with the piercer or center E¹⁴. This piercer or center E¹⁴ is formed with a cylindrical portion e⁸⁷ which is slidably fitted into the bore of the hub portion of said forming-die and centrally supports said 85 forming-die. Said piercer or center E¹⁴ is also formed with a tapered portion e⁸⁹ on which the work-piece is adapted to be supported and, with a cylindrical end portion e⁴⁰ which is slidably fitted into a central 90 bore e⁴¹ formed in the center E¹³ of the other supporting head M, as shown. The axle E of the supporting head M is provided with the center E¹³ which has at its outer end next to the work-piece a central bore 95 e⁴¹ slidable over the end portion e⁴⁰ of said piercer or center E¹⁴, as shown. The outer end face of this center E¹³ adjacent the work-piece is formed straight and the diameter of said end face of said center is 100 the same or is less than the smallest diameter which the hub at the side of the work-piece adjacent said center is to have when finished. The peripheral face of said center E¹³ is preferably formed conical so as to 105 permit the end face of the roll J¹, as shown, to properly come in contact with said peripheral face during the operating process for rolling or forming the hub. The forming-die W⁶, the die-supporting roll G¹⁴, and the 110 edging and die-supporting roll J⁶¹, are moved and adjusted into the proper positions, as for instance shown in Fig. 51, and therein they are rotatably retained during 115 the operating process. In such positions, the roll G¹⁴ is supporting the forming-die with its die-supporting portion g¹³⁹ in both radial and lateral or axial directions and, with its edging or supporting portion g¹³⁷ it is against or in contact with the face finishing roll H as shown, and the roll J⁶¹ is supporting the forming-die with its die-supporting portion j⁴⁰, in both radial and lateral or axial directions and with its edging roll portion j²⁹ it is against or in 120 contact with the face rolling roll K, as shown. Said die-supporting portion j⁴⁰ of said roll J⁶¹, or the edging roll portion j²⁹ of said roll J⁶¹ may be rotated or driven by 125 its shaft J and the other part or parts of 130

this roll may be made in a separate part or parts which are permitted to turn loose on a journal or journals provided on said roll J^{61} or on its said shaft J .

5 In the operation illustrated in Fig. 51, the face roll H is moved a certain radial distance away from the periphery of the forming-die W^6 , as shown, and the face roll K is against or in contact with the peripheral 0 edge of the forming-die W^6 , as shown. The supporting head M^{50} with its axle E and piercer or center E^{14} are moved, by the means before described, into the positions shown by the dotted lines, after which the 5 work-piece F is brought into the position shown and said parts M^{50} , E and E^{14} are again moved, by the means before described, which positions said parts M^{50} , E and E^{14} the edging roll portion j^{29} of said roll J^{61} 0 are retained until the work-piece is ready to be dished. The center E^{13} of the axle E and supporting head M is then moved, by the said power or pressure means operatively connected with said head M , over 5 said end part e^{40} of said piercer or center E^{14} and against one side of the work-piece F , while simultaneously therewith the roll J^1 is forced or rolled into said side of the work-piece and thus forces metal of the 0 work-piece at its other side into the hub-forming cavity of said forming-die W^6 and around the portion e^{29} of said piercer or center E^{14} , thus forming the hub at both sides of the work-piece, as shown in Fig. 52. During such action and while the work-piece is increasing in diameter, the face roll K is moving away from the periphery of the forming-die W^6 and metal of the work-piece is forced over said inclined peripheral 5 face w^8 of said forming-die W^6 and against the edging roll portion j^{29} of said roll J^{61} as shown in Fig. 52. In this manner the work-piece is rolled or formed to the form shown at F in Fig. 52. During the entire process, the edging roll portion j^{29} of roll J^1 is acting against or in contact with the portion of the work-piece between the web rolling part j^{28} of said roll J^1 and the periphery of the work-piece at one side thereof, as shown, and the edging roll portion j^{29} of roll J^{61} is acting against or in contact with the other side of the marginal or rim portion of the work-piece, as shown.

Fig. 52 shows said work-piece F rotatably supported and so rolled or formed to the form shown, with its hub completely formed and with the outer end face of roll J^1 in contact with or against the peripheral face of said center E^{13} , and also with the roll J^1 forced into the work-piece at one side thereof and with one side of the work-piece against said forming-die W^6 as shown. With the parts thus positioned, the web portion of the work-piece may be reduced or rolled and formed to its desired thickness in the follow-

ing manner, forming part of said rolling or forming process or steps:—Said roll J^1 , while operating against the work-piece at one side thereof, may be moved, during the rolling or forming process, longitudinally 70 or substantially so from its position adjacent the hub portion, shown in solid lines in Fig. 52 and in dotted lines in Fig. 53, to the position adjacent the rim portion shown in Fig. 53, and during said longitudinal movement or movements of said roll J^1 , the web reducing roll portion j^{28} of said roll J^1 is rolling or reducing the thickness of the web portion of the work-piece to its desired thickness and is rolling or forming 75 the inner peripheral face of the rim of the work-piece at one side thereof to the rudimentary form shown, and also forcing metal of the work-piece over said sufficiently inclined peripheral face w^8 of the forming-die 80 W^6 , thereby forming the inner peripheral face of the work-piece at the other side thereof to the sufficiently inclined rudimentary form shown, and as and for the purpose hereinbefore described with reference for 85 instance to Figs. 113 and 114; or said roll J^1 when rolling said web portion to its desired thickness, may be moved longitudinally forward and backward as often as desired. Simultaneously with the longitudinal movements of said roll J^1 , said face roll K is against or is operating against the peripheral face of the work-piece and rolls the same to the said beaked or rudimentary form, as shown for instance in Figs. 53 and 90 100 105 110 115 120 125 130 113. While the roll parts j^{28} , j^{29} of said rolls J^1 , J^{61} are still operating in contact with the lateral sides of the rim portion, said finishing rolls G^1 and H , shown at the other side of the axis of the work-piece, begin operating against the so rudimentarily formed rim portion and roll with said roll G^1 the so rudimentarily rolled inner peripheral face of the rim of the work-piece at one side thereof to the finished form and roll with said roll H the so beaked or rudimentarily formed peripheral face of the work-piece to the finished form shown at F^2 , in Fig. 54. During this action, the edging roll parts j^{28} , j^{29} of said rolls J^1 , J^{61} are maintaining the lateral thickness of the rim to which the same has been rolled during the process, and simultaneously with the operations of said rolls G^1 and H against the work-piece, the dishing may be done to dish the work-piece 120 or wheel while the same is rotating to the form F^2 shown in Fig. 54; which dishing may be done in the same manner as before described, for instance with reference to Figs. 6 to 16, that is:—while either, any or all the driven 125 or all the rolls are in operation, and while the said rolls G^{14} , J^{61} and forming-die W^6 are retained in fixed rotatable positions, as shown, and while the marginal or rim portion of the work-piece is in contact with the 130

forming-die W^6 by reason of pressure being applied thereagainst by, for instance, the roll J^1 , the constant pressure acting against said power or pressure mechanism operatively connected with the supporting head M is gradually somewhat relieved or reduced, retaining therein however the constant pressure required to retain the aforesaid axially clamped condition of the hub or 5 center portion of the work-piece between said centers E^{13} , E^{14} , thereby causing the pressure acting against the power or pressure mechanism operatively connected with the other supporting head M^{50} to overcome 10 the resistance of the supporting head M and gradually moving said heads M , M^{50} with the center or hub portion of the work-piece or wheel axially into the position of the dished wheel shown at F^2 in Fig. 54. While 15 thus effecting the dishing, the work-piece or wheel together with the forming-die W^6 are rotating and the marginal or rim portion of the work-piece or wheel is laterally supported and retained by said forming-die W^6 20 and said roll J^1 , or by said forming-die W^6 and both said rolls J^1 and G^1 against said axial movement of said center or hub portion. It is to be noted that the center or hub 25 portion of the work-piece or wheel, during this dishing or dishing and rolling process, is firmly held in said automatically clamped condition between said centers E^{13} , E^{14} while 30 said centers and said forming-die W^6 are rotating with the work-piece or wheel. The work-piece or wheel shown at F^3 in Fig. 54 35 is finished and may be removed by moving the rolls J^1 , G^1 , K and H into the positions shown for instance in Fig. 51 and by moving said supporting head M^{50} with its axle E 40 and piercer or center E^{14} into the position shown in dotted lines in Fig. 51, when the work-piece or finished product may be taken out and replaced by another work-piece, &c. Said dishing can also be done in the manner 45 hereinbefore described under "Dishing."

It is to be noted that during the entire rolling or forming and dishing operations, said centers E^{13} , E^{14} are kept in line by the cylindrical end portion e^{40} of said piercer or center E^{14} being held by said central hole e^{41} of said center E^{13} , and while so connected with each other and when the work-piece has been formed during the hub forming process to the form shown in Fig. 52, said 50 centers E^{13} , E^{14} are also forced against the opposite sides of the work-piece as shown in the Figs. 52, 53 and 54, thereby forming one substantial supporting device which is absolutely required in cases where such long 55 piercer or center is to be used.

In rolling for instance the peripheral face of car wheels or similar articles first to a beaked or rudimentary shape simultaneously with the rolling or forming of the 60 rim portion to the rudimentary form shown

for instance in Figs. 53, 66 and 113 and as and for the purpose hereinbefore described with reference to the Figs. 113 and 114, and then to the finished form; the tread or face rolling roll K with its peripheral face 70 formed for instance as shown in Fig. 55, 66 or 113, &c., or a similar face, serves to beak the peripheral face of the work-piece or car wheel before rolling the same to finished form; that is, said roll K serves 75 to preliminarily roll the peripheral face of the work-piece or wheel to beaked or rudimentary shape, for instance, to forms such as shown in the Fig. 118, 119, 120 or 121, or to other rudimentary forms; such preliminary actions being herein termed "beaking". During such beaking and rolling or forming process the metal in the whole rim portion of the work-piece or wheel is worked continually and simultaneously upon all its 80 surfaces, which gives the metal forming the tread, flange, and the whole rim portion of the work-piece or wheel the required uniform strength and density absolutely necessary for maximum and uniform resistance 85 to wear. After this beaking action is completed, the finishing roll or rolls are brought into action and roll said beaked or rudimentarily formed peripheral face to the finished shape of the tread and flange of the 90 wheel and roll the same to its desired finished diameter as, for instance, shown by the dotted lines f^{12} for said finished peripheral face in Figs. 118, 119, 120 and 121, and diagrammatically illustrated in the Figs. 100 113 and 114, whereby the metal in the tread and flange and the whole rim portion is still further condensed. The car wheel thus rolled or formed in accordance with my invention has its metal uniformly condensed 105 to its maximum where it is subjected to greatest strain and wear, and at the point heretofore considered the weakest.

A car wheel or other circular article may also be rolled or formed, as for instance 110 described in the following with reference to the Figs. 55 to 57, in which I have, for instance, illustrated in brief, a rolling or forming process or steps according to my invention, such as I prefer to employ for 115 completely rolling or forming car wheels, &c., including the rolling or forming of the end face of the hub at one side of the work-piece, directly with the edging and web rolling roll J^{69} , and also for dishing the car 120 wheel shown at F^2 in Fig. 57, from a blank or work-piece shown at F in Fig. 55 having, for instance, a conical central hole, as shown. In these figures the forming-die W^{14} is formed at one side with a central hub having 125 a bore of two diameters forming a shoulder. The axle E of the supporting head M^{50} is provided with the center E^{16} . This center E^{16} is formed with a cylindrical portion e^{38} and an enlarged cylindrical portion 130

or flange e^{27} , and at its outer straight-faced end adjacent the work-piece it has a central bore e^{44} , as shown. This center E^{16} is slidably fitted into said bore in the hub of said forming-die W^{14} , thus supporting said forming-die. The axle E of the supporting head M is provided with the piercer or center E^{15} . This piercer or center E^{15} has adjacent its axle-end a cylindrical or slightly tapered portion e^{42} , the peripheral face of this portion e^{42} being preferably formed conical so as to permit the end face of the roll J^{69} to properly come against or in contact with said peripheral face during the operating process for rolling or forming the hub, and next to said slightly tapered portion said piercer or center has a tapered portion e^{39} on which the work-piece F with its central hole is adapted to be supported. At the small diameter of said tapered portion e^{39} said piercer or center is formed with a shoulder as shown, and from said shoulder said piercer or center is formed with a cylindrical portion e^{45} having its end rounded off or formed as shown and which cylindrical portion e^{45} is fitted into the central bore e^{44} of said center E^{16} . During the operating process, said piercer or center E^{15} with its shoulder at the small diameter of its tapered portion e^{39} is pressing against the adjacent straight faced end of said center E^{16} and, said centers E^{15} and E^{16} are so retained with each other during the operating process, as shown. The forming-die W^{14} , the die-supporting roll G^{14} , and the edging and die-supporting roll J^{61} have been moved and adjusted into the proper positions, as for instance shown in Fig. 55, and they are rotatably retained in said positions during the operating process. When thus positioned, the roll G^{14} with its die-supporting portion g^{139} is supporting the forming-die in both radial and lateral or axial directions and, with its edging or supporting portion g^{137} it is against or in contact with the face finishing roll H as shown, and the roll J^{61} with its die-supporting portion j^{40} is supporting the forming-die in both radial and lateral or axial directions and, with its edging roll portion j^{29} it is against or in contact with the face rolling roll K , as shown. Said die-supporting portion j^{40} of said roll J^{61} , or the edging roll portion j^{29} of said roll J^{61} may be rotated or driven by its shaft J and the other part or parts of this roll may be made in a separate part or parts which are permitted to turn loose on a journal or journals provided on said roll J^{61} or on its said shaft J .

At the commencement of the process illustrated in Fig. 55, the face roll H is moved a certain radial distance away from the periphery of the forming-die W^{14} , as shown, and the face roll K is against or in contact with the peripheral edge of the forming-die W^{14} , as shown. The supporting head M with its axle E and piercer or center E^{15} are moved, by the means before described, into the positions shown by the dotted lines. The work-piece F is then brought into the position shown and said parts M , E and E^{15} are again moved, by the means before described, into the positions shown in Fig. 55, in which positions said parts M , E and E^{15} are retained until the work-piece is ready to be dished. In these figures, the edging and web rolling roll J^{69} is preferably formed as shown; that is, the part j^{28} of said roll J^{69} is the roll part adapted to roll or operate as shown upon the end face of the hub at one side of the work-piece and the part j^{26} of said roll J^{69} is said web reducing roll part, (which may however have any other desirable or suitable form or shape than herein shown), operating against part of the end face of the hub, the peripheral face of the hub and adjacent web part, the intermediate web part, and the inner peripheral face of the rim and adjacent web part of the work-piece at one side thereof. The part j^{29} of said roll J^{69} is the edging roll part operating upon and maintaining the lateral thickness of the rim and limiting therein the lateral flow of metal and operating against or in contact with the portion of the work-piece between said web reducing roll part j^{28} of said roll J^{69} and the periphery of the work-piece at its one side. While the work-piece is rotated by said roll J^{69} and said forming-die W^{14} , which forming-die may be rotated by either or both said rolls J^{61} , G^{14} , said roll J^{69} is forced or rolled into the side of the work-piece and thus forces metal of the work-piece at its other side into the hub-forming cavity of said forming-die W^{14} and around the portion e^{39} of said piercer or center E^{15} , thus forming the hub at both sides of the work-piece, as shown in Fig. 56. During this action and while the work-piece is increasing in diameter, the face roll K is moving away from the periphery of the forming-die W^{14} and metal of the work-piece is forced, by said roll J^{69} , over said inclined peripheral face w^3 of said forming-die W^{14} and against the edging roll portion j^{29} of said roll J^{61} , as shown in Fig. 56. The work-piece is thus rolled or formed to the form shown at F in Fig. 56. During the entire process the edging roll portion j^{29} of roll J^{69} is adapted to act against or in contact with the portion of the work-piece between the web rolling part j^{28} of said roll J^{69} and the periphery of the work-piece at one side thereof as shown and, the edging roll portion j^{29} of roll J^{61} is acting against or in contact with the other side of the marginal or rim portion of the work-piece, as shown. Fig. 56 shows said work-piece F rotatably

supported and so rolled or formed to the form shown, with its hub completely formed and with the outer end face of roll J^{69} in contact with or against the peripheral face 5 of said piercer or center E^{15} and, with the roll J^{69} forced into the work-piece at one side thereof and with one side of the work-piece against said forming-die W^{14} as shown. With the parts thus positioned, 10 the web portion of the work-piece may be reduced or rolled and formed to its desired thickness in a manner which is the same or similar to the manner as above described with reference to Figs. 52 and 53, that is:—

15 Said roll J^{69} may be moved during the web rolling or forming process longitudinally or substantially so from its position adjacent the hub portion, shown in Fig. 56, to the position of the roll J^1 adjacent the rim portion, shown for instance in Fig. 53, and during said longitudinal movement or movements of said roll J^{69} , the web reducing roll portion j^{28} of said roll J^{69} is also rolling or reducing the thickness of the web 20 portion of the work-piece between the part j^{28} of said roll J^{69} and the forming-die W^{14} to its desired thickness and is rolling or forming the inner peripheral face of the rim of the work-piece at one side thereof 25 to the rudimentary form shown and forcing metal of the work-piece at its other side over said sufficiently inclined peripheral face w^3 of the forming-die W^{14} , thereby forming also the inner peripheral face of 30 the work-piece at the other side thereof to the sufficiently inclined or rudimentary form shown, and as and for the purpose hereinbefore described with reference for instance to Figs. 113 and 114; or said roll 35 J^{69} when so rolling or forming said web portion to its desired thickness, may be moved longitudinally forward and backward as often as desired, while simultaneously with said longitudinal movements of 40 said roll J^{69} said face roll K is against or is operating against the peripheral face of the work-piece and rolls the same to the said beaked or rudimentary form, as shown for instance in Fig. 113. While the roll 45 parts j^{29} , j^{29} of said rolls J^{69} , J^{61} are still operating in contact with the opposite sides of the rim portion of the work-piece, said finished rolls G^1 and H , shown at the other side of the axis of the work-piece, begin 50 operating against the so rudimentarily formed rim portion, and roll with said roll G^1 the so rudimentarily rolled inner peripheral face of the rim of the work-piece at one side thereof to the finished form and roll 55 with said roll H the so beaked or rudimentarily formed peripheral face of the work-piece to the finished form shown at F^2 in Fig. 57. At the same time, the edging roll parts j^{29} , j^{29} of said rolls J^{69} , J^{61} are maintaining the lateral thickness of the rim to

which the same has been rolled during the process. Simultaneously with the operations of said rolls G^1 and H against the work-piece and while the work-piece or wheel is rotating, the dishing may be done 70 to dish the work-piece or wheel to the form F^2 shown in Fig. 57; which dishing may be done in the same manner as before described, for instance with reference to Figs. 6 to 16, that is:—While either, any or all 75 the driven or all the rolls are in operation, and while the said rolls G^{14} , J^{11} and forming-die W^{14} are retained in fixed rotatable positions, as shown, and with the marginal or rim portion of the work-piece in contact 80 with the forming-die W^{14} by reason of pressure being applied thereagainst by, for instance, the roll J^{69} , the constant pressure acting against said power or pressure mechanism operatively connected with the supporting head M is gradually somewhat relieved or reduced, retaining therein however the constant pressure required to retain the aforesaid axially clamped condition of the hub or center portion of the work-piece between said centers E^{15} , E^{16} , thereby causing the pressure acting against the power or pressure mechanism operatively connected with the other supporting head M^{50} to overcome the resistance of the supporting head M and gradually moving said heads M , M^{50} with the center or hub portion of the work-piece or wheel axially into the position of the dished wheel shown at F^2 in Fig. 57. During this dishing operation the work-piece or wheel, together with the forming-die W^{14} are rotating and the marginal or rim portion of the work-piece or wheel is laterally supported and retained by said forming-die W^{14} and said roll J^{69} , or by 100 said forming-die W^{14} and both said rolls J^{69} and G^1 against said axial movement of said center or hub portion. It is to be noted that the center or hub portion of the work-piece or wheel, during this dishing or dishing and rolling process, is firmly held in said automatically clamped condition between said centers E^{15} , E^{16} while said centers and said forming-die W^{14} are rotating with the work-piece or wheel. The work-piece or wheel shown at F^2 in Fig. 57 is finished and may be removed by moving the rolls J^{69} , G^1 , K and H into the positions shown for instance in Fig. 55 and by moving said supporting head M with its axle 110 E and piercer or center E^{15} into the position shown in dotted lines in Fig. 55. The work-piece or finished product taken out may be replaced by another work-piece, &c. Said dishing may also be done in the manner 115 hereinbefore described under "Dishing".

It is further to be noted that during the entire rolling or forming and dishing operations, said piercer or center E^{15} , and the center E^{16} are kept in line by said cylinder 120

drical end part e^{16} of said piercer or center E^{16} being held by said central hole e^{14} of said center E^{16} , and while so connected with each other are also forced against each other, 5 thereby forming one substantial supporting device which is absolutely required in cases where such long piercer or center is to be used.

A car wheel which is to be used, for instance, for light loads and light traffic only, 10 may be rolled or formed as for instance described in the following with reference to Figs. 58 to 60 inclusive, in which I have for instance illustrated in brief, rolling or 15 forming steps for completely rolling or forming and dishing the car wheel shown at F^2 in Fig. 60 from a blank or work-piece shown at F in Fig. 58, having for instance a conical or tapered central hole as shown. In 20 these figures the forming-die W^{19} is formed or shaped to conform to the center or hub part, the web part, the inner peripheral face of the rim portion, the lateral side of the rim of the finished car wheel at one side thereof 25 before it is dished and said die also conforms to the peripheral face or flanged tread of the finished car wheel; the other side; that is, one side only, of the work-piece or wheel being rolled or formed by rolls as 30 shown. In this process the metal in the peripheral face of the work-piece is not worked during the process, therefore the metal will be extended instead of being compressed, thereby producing incipient cracks 35 in the tread or outer peripheral face of the rim, as hereinbefore referred to, but wheels thus produced with the use of this forming-die W^{19} having the forming portion formed as shown in the Figs. 58 to 60, may be used 40 for light loads and light traffic only. The operating process in said Figs. 58 to 60 for rolling and forming and for dishing the wheel is the same or similar to the operating process before described with reference to 45 Figs. 55 to 57 inclusive, with the exception that during the enlargement of the diameter 50 of the work-piece during the operating process of forming the rim portion of the work-piece or wheel, the metal at the peripheral face of the work-piece is not worked and in this process the tread or face rolls K and H are not used to operate against the work-piece but they are used for supporting the forming-die W^{19} at its peripheral face in 55 both lateral and opposite radial directions; that is, the peripheral face of said forming-die at or near its ends is formed straight with a circumferential track or groove w^6 between said straight ends, and, the face roll K at its peripheral portion is correspondingly shaped with the tongue portion K^{19} and straight-faced portions to fit said circumferential groove w^6 and said straight-faced portion of the forming-die W^{19} . The 60 face roll H at its peripheral portion is cor-

respondingly shaped with the tongue portion H^{19} and straight-faced portions to fit said groove w^6 and said straight-faced portion of the forming-die W^{19} as shown. The edging and die-supporting roll J^{19} and die-supporting roll G^{109} are in this case serving the only purpose to support the forming-die and are shown with stepped portions, each step-portion having its peripheral face formed straight, or approximately so, and the side of 75 the forming-die next to said rolls J^{19} , G^{109} is correspondingly shaped to fit said stepped portions of said rolls J^{19} , G^{109} , thereby supporting said forming-die W^{19} in both lateral and opposite radial directions. 80

It is also to be observed that in this process, the edging roll portion g^{187} of the roll G^{55} as well as the edging roll portion j^{19} of the roll J^{19} is adapted to operate against the side of the rim of the work-piece or 85 wheel and roll the same to its desired width as shown, and that, during the web reducing operation of the work-piece said roll J^{19} may be moved longitudinally between the hub and rim portions of the work-piece, forward or backward, or forward and backward as often as desired.

In Fig. 61 the wheel shown at F^2 is rolled or formed and dished with the use of the same forming-die W^{19} , and the same rolls 95 H , K , J^{19} and J^{19} shown in Figs. 58 to 60, but in this process the rolls G^{55} and G^{109} shown in Figs. 58 to 60 are not used. The wheel is rolled or formed with only the use of the rolls shown and it is rolled or formed 100 and dished in a similar manner as described with reference to Figs. 58 to 60, except without the rolls G^{55} and G^{109} .

In the Figs. 62 and 63, the work-piece F is similar to the work-piece F in the Figs. 105 55 and 58, and the axle E and piercer or center E^{16} with the supporting head M and the axle E and center E^{16} with the supporting head M^{16} are all the same and may be operated in the same manner as before described with reference to Figs. 55 to 61 inclusive, and the roll J^{19} is the same and 110 may be operated in the same manner as before described with reference to Figs. 55 to 61. The roll G^1 is also the same and 115 may be operated in the same manner as before described with reference to Figs. 51 to 57 and the roll J^{19} is similarly formed and serves the same purpose as roll J^{19} in Figs. 58 to 61. The roll G^{110} is also similarly 120 formed and serves the same purpose as roll G^{109} in Figs. 58 to 60. In these Figs. 62 and 63, however, the forming-die W^{20} is formed differently; that is, the circumference or periphery of the forming portion 125 of this die W^{20} reaches to a circle which has a diameter equivalent to that portion of the finished side of the rim of the work-piece or wheel where the rounding off of the outer circumferential corner of the 130

42

tread commences and at this circle the forming-die W^{20} is formed with a circular off-set or shoulder w' , and the tread or face finishing roll H has its peripheral or rolling face H^1 formed as shown with a circular flange h^{11} provided with a fillet formed correspondingly with the rounded corner of said tread. When this face roll H is properly positioned at a certain radial distance 10 from the axes of the piercer or center E^{15} , and the center E^{16} , the outer diameter of said flange h^{11} is in contact with said shoulder w' of said forming-die W^{20} as shown in Fig. 62. This one side of the 15 rim of the work-piece or wheel is therefore formed by the forming-die, and the peripheral face of the work-piece or wheel including its flange and the rounding off of the outer corner of the tread of the rim 20 is rolled to finish with said roll H , as shown. The face beaking or face rolling roll K has its peripheral or rolling face K^1 formed as shown and at its side next to forming-die W^{20} said roll K is formed or 25 provided with the circular portion or extension K^{11} as shown. At the commencement of operation, the roll K with its rolling face K^1 is moved against the peripheral portion w' of said die W^{20} as shown in Fig. 30 30. When the roll K is thus positioned the circular portion K^{11} of said roll K may be in contact with or be somewhat away from the shoulder w' of said die W^{20} , as shown in Fig. 62, thereby, during the operating 35 process and while said roll K moves from the position thereof shown in Fig. 62 to the position thereof shown in Fig. 63, the one side of said roll K will be fully supported by said forming-die W^{20} , as shown. 40 At the same time, the other side of said roll K will be against or in contact with the edging roll portion j^{20} of said roll J^{20} and thus one side of the rim portion of the work-piece or wheel is being formed by said 45 forming-die while the other side of said rim portion is being rolled to the desired width of said rim portion by the edging roll portion j^{20} of said roll J^{20} , as shown in Fig. 63. In this process, said face roll H is positioned at the proper radial distance from 50 the axis of said piercer or center E^{15} and said center E^{16} to suit the finished radius of the finished wheel and it is retained in said position during the rolling or forming 55 and dishing operations. Otherwise the operating process or steps is similar to the operating process or steps before described with reference to Figs. 55 to 57.

A car wheel or other circular article may 60 also be rolled or formed as for instance described in the following with reference to the Figs. 64 to 67, in which the roll J^{20} may be the same and may be operated the same or similar to the roll J^{20} described 65 with reference to Figs. 55 to 57 and Figs.

62 and 63, and the roll J^{21} may be the same and may be operated the same or similar to the roll J^{21} described with reference to Figs. 51 to 57 inclusive, and the roll G^1 may be the same and may be operated the 70 same or similar to the roll G^1 described for instance with reference to Figs. 51 to 57 and Figs. 62 and 63 and the roll G^{14} may be the same and may be operated the same or similar to the roll G^{14} described 75 for instance with reference to Figs. 51 to 57. In these Figs. 64 to 67 inclusive, I have illustrated in brief, a rolling or forming operation or steps, according to my invention, such as I prefer to employ for 80 completely rolling or forming and dishing the car wheel shown at F^2 in Fig. 67, including the rolling of the entire end face of the hub of the work-piece at one side thereof and the piercing or penetrating or 85 centering of the properly heated work-piece from a blank or work-piece, such as shown at F in Fig. 64, in which figure the work-piece F and the forming-die W^{12} are shown in diametral section and the work-piece 90 may have a thickness which is either the same or greater, or less than the length which the hub of the car wheel is to have when rolled or formed to finish.

Fig. 64 shows said work-piece F brought 95 into the position shown by said positioning, or raising, lowering and retaining device, and in this position the outer portion or periphery of the work-piece is coaxial, or approximately so, with the piercers or centers E^1 , E^2 and central with the forming-die W^{12} . In this case, said piercers or centers are formed as shown and the lengths of their penetrating portions e^{12} , e^{13} are made to suit the location of the web portion of the 100 car wheel as shown; that is, the web portion of the wheel in this case will be formed in the center of the length of the hub of the wheel and said penetrating portions of said piercers or centers E^1 , E^2 will have both the 105 same length, which may reach to or near the center of the thickness of the finished web adjacent the hub portion of the wheel, as shown in Fig. 66. The forming-die W^{12} is formed or shaped at its forming-side to conform to the center or hub part, the web part, and the inner peripheral face of the rim of the finished car wheel at one side thereof 110 before being dished, as shown. At its other side next to the rolls G^{14} , G^{21} this forming-die is formed with a central hub having a bore of two diameters so as to form a shoulder and is formed with a circular track 115 or groove w' as shown. The axle E of the supporting head M^{20} is provided with the 120 piercer or center E^2 which is formed with a cylindrical portion e^{26} and an enlarged cylindrical portion or flange e^{27} and at its outer end adjacent the work-piece it is provided with the piercing or penetrating or 125 130

forming portion e^{29} . The portions e^{27} , e^{28} of said piercer or center E^1 are slidably fitted in the bore of the hub of said forming-die W^{12} , thus supporting said forming-die. The 5 axle E of the supporting head M is provided with the piercer or center E^1 . This piercer or center E^1 is formed adjacent its piercing or penetrating or centering part e^{29} with an extension e^{42} having a straight or approximately straight peripheral face, the diameter at the adjoining portions of said extension and said piercing or penetrating or centering part being the same or substantially the same. The peripheral face of the 10 extension e^{42} of said piercer or center E^1 is formed cylindrical or slightly conical so as to permit the end face of the roll J^{69} to properly come against or in contact therewith during the operating process for rolling or forming the hub as shown in Figs. 64 and 65. The forming-die W^{12} , the die-supporting roll G^{14} , and the edging and die-supporting roll J^{61} have been moved and adjusted, by the means before described, into 15 the proper positions shown in Fig. 64 and therein they are rotatably retained during the operating process. When thus positioned, the roll G^{14} with its die-supporting portion g^{189} is supporting the forming die W^{12} in both radial and lateral or axial directions and with its edging or supporting portion g^{187} it is against or in contact with the face finishing roll H , as shown; the roll J^{61} with its die-supporting portion j^{40} is supporting the forming-die W^{12} in both radial and lateral or axial directions and with its edging roll portion j^{29} it is against or in contact with the face rolling roll K as shown. The die-supporting portion j^{40} of said roll 20 J^{61} , or the edging roll portion j^{29} of said roll J^{61} may be rotated or driven by its shaft J and the other part or parts of this roll may be made in a separate part or parts which are permitted to turn loose on a journal or journals provided on said roll J^{61} or on its shaft J .

At the commencement of the process illustrated in Fig. 64, the face roll H is moved to a certain radial distance away from the periphery of the forming-die W^{12} , as shown; the face roll K is against or in contact with the peripheral edge of the forming-die W^{12} , as shown; and the work-piece F is brought into the position shown. The piercer or center E^1 is retained in the position shown in Fig. 64 until the work-piece or wheel is ready to be dished. In this operating process, the edging and web rolling roll J^{69} is preferably formed as shown; that is, the peripheral or operating face of the roll part j^{29} of said roll J^{69} is formed substantially straight as shown and is the roll part adapted to roll or operate, as shown, upon the end face of the hub of the work-piece at one 25 side thereof during the rolling or forming

process of rolling or forming the hub of the work-piece. The part j^{28} of said roll J^{69} is the web reducing roll part, which may however have any other desirable or suitable form or shapes than herein shown, operating as shown alternately against the hub and adjacent web part, the web intermediate part, and the inner peripheral face of the rim and adjacent web part of the work-piece or wheel at one side thereof; that is, the web reducing roll part j^{28} of said roll J^{69} is operating with its outer rolling or operating portion upon the web and the hub parts of the work-piece at one side thereof and is forcing metal of the work-piece at its 30 other side into the hub-forming cavity of said forming-die W^{12} and around the penetrating or forming portion e^{29} of said piercer or center E^1 , thereby forming or shaping the hub at both sides of the work-piece as shown in Fig. 65. While the work-piece is increasing in diameter during the hub forming process and while the face roll K is moving away from the periphery of the forming-die W^{12} , metal of the work-piece is forced by said roll J^{69} over the inclined peripheral face w^3 of said forming-die and against the edging roll portion j^{29} of said roll J^{61} . During the web rolling or forming process, the inner rolling or operating portion of the part j^{28} of said roll J^{69} is operating on the web part and the inner peripheral face of the rim of the work-piece at one side thereof and rolls or forms said inner peripheral face of said rim at one side 35 of the work-piece to rudimentary form and sufficiently inclined toward the periphery of the work-piece as shown and also forces metal of the work-piece, at its other side, over said sufficiently inclined peripheral 40 face w^3 of the forming-die W^{12} , thereby forming also the inner peripheral face of the work-piece at the other side thereof sufficiently inclined toward the periphery of the work-piece, as shown. The peripheral 45 or operating face of the edging roll parts j^{29} , j^{28} of said rolls J^{69} , J^{61} are formed substantially straight, as shown, and during the rolling or forming process come in contact with or against the opposite sides of the 50 tread or face roll K , as shown. This edging roll part j^{29} of roll J^{69} is adapted to roll or limit the lateral flow of metal in the portion of the work-piece between the roll part j^{28} of said roll J^{69} and the periphery of the 55 work-piece; or such rolls, as for instance J^{69} , may not have such web reducing roll part j^{28} but be for instance wholly formed conical, as for instance shown at J^6 in Figs. 23 and 49, and as shown and described in my 60 said original application.

Fig. 65 shows the hub portion of the work-piece so rolled or formed as above described and with the edging roll portions j^{29} , j^{28} of the rolls J^{69} , J^{61} against or in contact 65

with the opposite sides of the face roll K; the lateral width or thickness of said face roll K is the same as the lateral width which the marginal or rim portion of the work-piece or wheel is to have when rolled or formed to finish, as shown in Figs. 65, 66 and 67. With the roll J⁶⁰ thus positioned, as shown in solid lines in Fig. 65 and in dotted lines in Fig. 66, and with the work-piece with its one side against the forming-die W¹², as shown, the web portion of the work-piece may be reduced or rolled and formed to the desired thickness in a manner which may be the same or similar to the manner as for instance before described with reference for instance to Figs. 52 and 53, that is: said roll J⁶⁰ may be moved during the web rolling or forming process longitudinally or substantially so from its position adjacent the hub portion, shown in solid lines in Fig. 65 and in dotted lines in Fig. 66, to the position of said roll J⁶⁰ adjacent the rim portion, shown in Fig. 66, and during the longitudinal movement or movements of said roll J⁶⁰, the web reducing roll portion j²⁹ of said roll J⁶⁰ is also rolling or reducing the thickness of the web portion of the work-piece between the part j²⁸ of said roll J⁶⁰ and the forming-die W¹² to its desired thickness and is rolling or forming the inner peripheral face of the rim of the work-piece at one side thereof to the said rudimentary form and it is also forcing metal of the work-piece at its other side over said sufficiently inclined peripheral face w² of the forming-die W¹² thereby forming also the inner peripheral face of the work-piece at the other side thereof to the sufficiently inclined form shown, and as and for the purpose before described with reference for instance to Figs. 113 and 114; or said roll J⁶⁰ when rolling or forming said web portion to its desired thickness, may be moved longitudinally forward or backward, or forward and backward as often as desired, while simultaneously with said longitudinal movements of said roll J⁶⁰ said face roll K is against or is operating against the peripheral face of the work-piece and rolls the same to the said beaked or rudimentary form, as and for the purpose shown and described for instance with reference to Fig. 113. While the edging roll parts j²⁹, j³⁰ of said rolls J⁶⁰, J⁶¹ are still operating in contact with the opposite sides of the rim portion of the work-piece, said finishing rolls G¹ and H, shown at the other side of the axis of the work-piece, begin operating against the so rudimentarily formed rim portion and, roll with said roll G¹ the so rudimentarily rolled inner peripheral face of the rim of the work-piece at one side thereof to the finished form while said roll H rolls the so beaked or rudimentarily formed peripheral face of the work-piece

to the finished form shown at F² in Fig. 67. At the same time, the edging roll parts j²⁹, j³⁰ of said rolls J⁶⁰, J⁶¹ are maintaining the lateral thickness of the rim to which the same has been rolled during the process. 70 Simultaneously with the operations of said rolls G¹ and H against the work-piece and while the work-piece or wheel is rotating, the dishing may be done to dish the work-piece or wheel to the form F² shown in Fig. 75 67, which dishing may be done in the same manner as before described, for instance with reference to Figs. 6 to 16; that is, while either, any or all the driven or all the rolls are in operation, and while the said rolls G¹⁴, 80 J⁶¹ and forming-die W¹² are retained in said fixed rotatable positions, as shown, and while the marginal or rim portion of the work-piece is in contact with forming-die W¹² by reason of pressure being applied 85 thereagainst by, for instance the roll J⁶⁰, the constant pressure acting against said power or pressure mechanism operatively connected with the supporting head M is gradually somewhat relieved or reduced, retaining therein however the constant pressure required to retain the aforesaid axially clamped condition of the hub or center portion of the work-piece between said piercers or centers E¹, E², thereby causing 90 the pressure acting against the power or pressure mechanism operatively connected with the other supporting head M⁶⁰ to overcome the resistance of the supporting head M and gradually moving said heads M, M⁶⁰ 100 with the center or hub portion of the work-piece or wheel axially into the position of the dished wheel shown at F² in Fig. 67. During this dishing operation, the work-piece or wheel, together with the forming-die W¹², are rotating and the marginal or rim portion of the work-piece or wheel is laterally supported and retained by said forming-die W¹² and said roll J⁶⁰, or by 105 said forming-die W¹² and both said rolls J⁶⁰ and G¹ against said axial movement of said center or hub portion. It is to be noted that the center or hub portion of the work-piece or wheel, during this dishing or dishing and rolling process, is firmly held in 110 said automatically clamped condition between said piercers or centers E¹, E² while said piercers or centers and said forming-die W¹² are rotating with the work-piece or wheel. The work-piece or wheel shown at F² in Fig. 67 is thus finished and may be removed by moving said rolls J⁶⁰, G¹, K and H and said supporting head M with its axle E and piercer or center E¹ into the positions shown for instance in Fig. 8 or 12. 115 120 Said dishing may also be done in the manner before described under "Dishing." 125 A car wheel or other circular article may 130

also be rolled or formed as for instance illustrated in the Figs. 79 to 83 inclusive, in which I have shown a car wheel or similar body rolled or formed from a solid circular blank shown at F in Fig. 79. The piercing or penetrating or centering process is similar to the process before described for instance with reference to Figs. 64 and 65, with the exception that in this case the 5 piercer or center, for instance E^o of the supporting head M, is provided with the flange or shoulder e^o, as shown; all other parts are similar to the corresponding parts shown in Figs. 64 to 67, with the exception that in 10 this case the edging and die-supporting roll J^o is formed somewhat different, and the hub end-face rolling portion j^o of the roll J^o is omitted in the roll J¹ shown in Fig. 79 and in place of said hub end-face rolling portion j^o the piercer or center E^o is provided with said flange or shoulder e^o, which 15 may serve the same purpose as said portion j^o. Otherwise the operation or steps illustrated in Figs. 79 to 82 inclusive may be the 20 same or similar to the operation or steps for instance described with reference to Figs. 64 to 67 inclusive. Fig. 79 shows the work-piece and the operating parts at or before commencement of operation. Fig. 80 shows 25 the work-piece and the operating parts at the end of the hub forming operation. Fig. 81 shows the work-piece and the operating parts at the end of the web forming and rim forming operation. Fig. 82 shows the 30 work-piece and the operating parts at the end of the rolling or forming and dishing operation. Fig. 83 shows side rolls substituted for the forming-die and its supporting rolls as shown, and with the parts as shown 35 in Fig. 83 the car wheel may be dished, or dished and rolled after being rolled or formed to the form for instance shown in Fig. 81; that is to say, the dishing operation hereinbefore described for instance 40 with reference to Figs. 6, 7 and 8 may also be done as illustrated in Fig. 83 and as shown and described in my said original application; that is, when the work-piece or a 45 number of work-pieces have each been 50 rolled or formed to the shape shown at F¹ in Fig. 81, each may be taken out of the apparatus or mill and put into a soaking-pit or heating furnace to retain its proper heat, and the rolls G¹⁴, J^o, piercer or center E^o 55 and forming-die W¹ will then be removed from the apparatus or mill, and rolls, for instance J², G², and piercer or center; for instance E^o, put into the apparatus or mill in place of the removed parts. The work-piece or wheel, while rotating, will then be 60 dished or dished and rolled with the retained and the substitute piercer or center and rolls, as for instance illustrated in Fig. 83. The dishing will be done in a similar 65 manner as hereinbefore described with ref-

erence for instance to Figs. 6 and 7, and also as described in my said original application.

Fig. 85 shows a diametral section of a finished rolled or formed and dished car wheel similar to the car wheel shown at F² in Fig. 82 and taken on line 85—85 Fig. 86, showing the inner peripheral face f^o of the rim of the wheel at one side thereof formed by the forming-die portion w^o and the action of the roll portions j^o, j^o to said sufficiently inclined form, for instance f^o, as illustrated in Figs. 81, 82, 118 and 114, and the inner peripheral face f^o of the rim of the car wheel at the other side thereof is first rolled by the roll J¹ to the form shown in Fig. 81 and is then rolled by the roll G¹ during the finishing process illustrated in Figs. 82 and 114 to the finished form, for instance f^o, as illustrated in Figs. 82 and 114.

Fig. 87 shows both said inner peripheral faces rolled or formed to the forms f^o, f^o, as shown.

The operating parts and the operations illustrated in Figs. 89 and 90 are similar to the process and parts before described with reference to Figs. 81 and 82 and the total process or steps is similar to the process or steps before described with reference to Figs. 79 to 82 inclusive, with the exception that the inclination of the peripheral portion w^o of the forming-die W¹ is formed so as to form the inner peripheral face f^o of the finished car wheel to the form shown at F² in Fig. 87.

In Figs. 91 to 94, inclusive, I have for instance illustrated in brief, a rolling or forming process or steps according to my invention, such as I prefer to employ for completely rolling or forming the undished car wheel hereinbefore referred to and for instance shown at F² in Fig. 77, or a car wheel similar thereto, including the piercing or centering of the properly heated work-piece. The operating parts and the operation are somewhat different from the ones shown in Figs. 80 and 82. In Fig. 91 the work-piece is shown rolled or formed to the form shown at F with its hub completely formed as hereinbefore described and there-in is shown the edging roll parts j^o, j^o of the rolls J¹, J^o against or in contact with the opposite sides of the face roll K which has a lateral width which is the same as the lateral width which the marginal or rim portion of the work-piece or wheel is to have when finished. In said Figs. 91 to 94 inclusive, said car wheel has its web formed in undished position; that is, at right angles, or approximately so, with the axis of the wheel, but the hub of this wheel is not formed central to the web, but it is formed into the position required of a dished wheel; that is, the hub is in the same position as for instance the hub in Fig. 76 or 85. The piercing or penetrating or forming portion

100

105

110

115

120

125

130

of the piercers or centers E^e , E^{10} , in this case, are formed of uneven lengths; that is, they may reach to or near to the center of the thickness of the web adjacent the hub 5 of the work-piece or wheel, as shown. The piercing or penetrating or centering process is similar to the process before described for instance with reference to Figs. 64 and 65, with the exception that in this process 10 the piercer or center used, for instance E^e , of the supporting head M , is provided with the flange or shoulder e^{10} , as shown. The work-piece F in said Fig. 91 is forced with one side against the forming portion of the 15 forming-die W^e , which die is slidably mounted on the piercer or center E^{10} of the axle E of the supporting head M^{10} . The work-piece is thus rotatably supported at its center, or hub portion by both said 20 piercers or centers E^e , E^{10} , and the forming-die W^e and work-piece are rotating with each other. When so supported, the work-piece may also be automatically and firmly clamped between said piercers or centers E^e , 25 E^{10} , as and for the purpose hereinbefore described, and be so retained during the entire rolling or operating process until the finished rolled or formed wheel is ready to be removed.

30 With the work-piece F and the operating parts in the positions shown in Fig. 91, with the end face of the edging and web rolling roll J' against or in contact with the flange or shoulder e^{10} of said piercer or center E^e , and with the roll J' thus positioned, the web portion of the work-piece F may be reduced, or rolled or formed to its desired thickness in either of the following manners, forming part of this rolling or forming process or steps: For instance, said roll J' may either be moved longitudinally, or approximately so, during the web rolling or forming process from its position adjacent the hub portion shown 35 in Fig. 91, to the position adjacent the rim portion shown in Fig. 93, or said roll J' may be so moved, during said web rolling or forming process, between said hub and rim portions forward or backward, or forward and backward as often as desired and, 40 during said longitudinal movement or movements of said roll J' , the web reducing roll part j^{28} thereof is rolling or forming or reducing the web portion of the work-piece 45 between the part j^{28} of said roll J' and the forming-die W^e to its desired thickness and is rolling or forming the inner peripheral face of the rim of the work-piece at one side thereof to the rudimentary form shown 50 in Fig. 93 and as and for the purpose hereinbefore set forth with reference for instance to the Figs. 113 and 114, and during said web rolling or forming process said roll J' is also forcing metal of the work-piece at its other side over said sufficiently 55 inclined face w^e of the forming-die W^e , thereby forming the inner peripheral face of the work-piece at its other side thereof to the sufficiently inclined or rudimentary form shown in Fig. 93, and as and for the purpose hereinbefore described with reference to Figs. 113 and 114. During this action and while the work-piece is increasing in diameter, as indicated for instance in Figs. 91 and 93, the face roll K is moving 60 outward to conform to the increasing diameter while said face roll is continually operating against the peripheral face of the work-piece, and while metal of the work-piece is forced, by said roll J' , over the inclined peripheral face w^e of said forming-die W^e and against the edging roll portion j^{28} of said roll J^{10} , as shown in Fig. 93. The work-piece is thus rolled or formed to the form shown at F' in Fig. 93. During the 65 entire process, the edging roll portion j^{28} of the roll J' is adapted to act against or in contact with the portion of the work-piece between the web rolling portion j^{28} of said roll J' and the periphery of the work-piece 70 at one side thereof, as shown, and the edging roll portion j^{28} of roll J^{10} is acting against or in contact with the other side of the marginal or rim portion of the work-piece 75 as shown. Simultaneously with said longitudinal movement or movements of said roll J' , said face roll K is also beginning or is operating against the peripheral face of the work-piece and rolls the same to the beaked or rudimentary form shown in Fig. 93 and 80 as and for the purpose hereinbefore described with reference to Figs. 113 and 114; or, instead of said longitudinal movement of said roll J' from its position adjacent the hub portion to the position adjacent the rim portion, said roll J' may be moved longitudinally, or approximately so, forward and backward as often as desired while simultaneously with said longitudinal movements of said roll J' , said face roll K is against 85 or is operating against the peripheral face of the work-piece and rolls the same to the said beaked or rudimentary form, as shown in Fig. 93. While the roll parts j^{28} , j^{28} , of 90 said rolls J' , J^{10} are still operating in contact with the lateral sides of the marginal or rim portion, said finishing roll G' shown at the other side of the axis of the work-piece is then moved laterally from its position shown in Fig. 93 to the position thereof 95 shown in Fig. 94 and, during its said lateral movement, it is rolling the so rudimentarily rolled inner peripheral face of the rim of the work-piece at one side thereof to the finished form. Simultaneously with the 100 operation of said roll G' against the work-piece at one side thereof, the face finishing roll H begins operating against the so beaked or rudimentarily formed peripheral face of the work-piece and rolls the same 105 110 115 120 125 130

to the finished form shown at F^2 in Fig. 94, while the edging roll parts j^{29} , j^{29} of said rolls J^1 , J^{29} are maintaining the lateral thickness of the rim to which the same has 5 been rolled during the process, thus finishing the wheel to the form F^2 shown in Fig. 94, or, if desired, said roll J^1 may, for instance, be retained in its position adjacent the hub portion of the work-piece F shown 10 in Fig. 91 and the web and the inner circumferential face of the rim of the work-piece at one side thereof, and the so beaked rudimentarily formed peripheral face of said rim portion of the work-piece may be rolled 15 or formed with the rolls G^1 , H and the forming-die W^1 by moving the roll G^1 from its position shown in Fig. 91 to the position thereof shown in Fig. 92 and, during said lateral movement said roll G^1 is reducing 20 or rolling or forming the unfinished portion of the web of the work-piece to its desired thickness and the inner peripheral face of the rim of the work-piece at one side thereof to the finished form shown, while 25 simultaneously with the operation of said roll G^1 against the work-piece, said finishing roll H may be in contact with or begin operation against the so beaked or rudimentarily formed peripheral face of the work-piece 30 and roll the same to the finished form shown at F^2 in Fig. 92, while the roll parts j^{29} , j^{29} of said rolls J^1 , J^{29} are maintaining the lateral thickness or width of the rim to which the same has been rolled during the 35 process, thus having finished the wheel to the form F^2 shown in Fig. 92. In this manner the wheel is rolled or formed perfectly true and smooth, to balance, and to gage or gages. Any surplus of metal in the work-piece or car wheel may be forced, during the 40 rolling or forming process, to flow either into the inner rim and adjacent web portion, that is to say, into the space indicated by f^{13} in Fig. 94, or it may be forced into 45 any other portion or portions of the work-piece, wheel or other object, without leaving a raised undesirable circular portion or fin anywhere on the finished rolled wheel.

By such rolling or forming process or 50 steps, according to my invention, as for instance above described and illustrated in Figs. 91 to 94 inclusive, for completely rolling or forming car wheels or other circular bodies, including said piercing or penetrat- 55 ing or centering of the work-piece, with my said preferred means, a solid blank or work-piece, as for instance shown at F in former Fig. 64, is pierced or penetrated or centered, as hereinbefore set forth, and may be completely rolled or formed with one heat in the 60 same apparatus or mill to the completely rolled or formed finished car wheel shown at F^2 in the Fig. 92 or 94.

Figs. 95 and 96 illustrate a dished disk- 65 wheel, or a center such as for instance used

in some tired car wheels. In these figures the peripheral rolling or operating face K^1 of the face rolling roll K is formed straight, and the peripheral rolling or operating face H^2 of the face finishing roll H is also formed 70 straight. These face rolls K and H may be connected together by means of said equalizing mechanism hereinbefore described with reference to Fig. 1 or 5 or when so connected 75 may be disconnected from said equalizing mechanism without disconnecting said rolls from their power or pressure means; that is to say, said face rolls K and H may be operated against the peripheral face of the work-piece either together in unison, or independent of each other. In Fig. 95 the work-piece has been rolled or formed, including 80 its web portion, to the form shown at F^1 , in a similar manner as hereinbefore described and, with the operating parts shown in the 85 positions at beginning of the dishing or dishing and rolling operations. In Fig. 96 the work-piece has been dished or dished and rolled to the form shown at F^2 in a similar manner as hereinbefore described 90 and, with the operating parts shown in the positions at the end of the finishing and dishing operations.

In Figs. 97 and 98 is illustrated, for instance, a new or worn car wheel rolled, for 95 instance, smaller in diameter. In this case the actual forming portion of the preferred forming-die reaches to the inner peripheral face of the rim of a car wheel at one side thereof when rolled or formed to its desired 100 finished smaller diameter and it is shaped to conform to the dished web portion, the center or hub part and the inner peripheral or inner circumferential face of the rim portion of the car wheel at one side thereof 105 when rolled or formed to its desired finished smaller diameter. The piercing or penetrating or forming portion w^1 is formed integral with the forming-die W^1 , as shown. Fig. 97 shows the work-piece F^1 placed onto the 110 forming-die W^1 and the operating parts in the positions they assume at the beginning of operation against the rim portion of the work-piece F^1 , and it also shows the center w^1 of the forming-die W^1 and the 115 center E^1 of the axle E of the supporting head M forced or entered loosely into the central hole and over the peripheral face of the hub portion of the work-piece F^1 , that is, the center w^1 of the forming-die is 120 either forced or entered loosely into the bore and at the same time the peripheral face of the hub of the work-piece at the side next to the forming-die is forced into the hub-forming cavity of the forming-die, and the 125 center part e^{26} of the center E^1 is either forced or entered loosely into the bore while the flange part e^{25} thereof which surrounds said center part e^{26} and is formed integral with said center E^1 is forced over the 130

peripheral face of the hub portion of the work-piece at the other side thereof, thus making the hole in the work-piece, or a part or parts thereof, either larger or smaller 5 in diameter so the wheel when finished may be rebored to its original diameter or to a larger diameter. The space or distance between the inclined peripheral face w^s of the forming-die W^s and the inner 10 peripheral face of the rim of the work-piece at one side thereof, indicated by f^{2s} , will be filled up with metal of the rim and adjacent web portion during this process, as shown in Fig. 98. In this case, the rolling 15 or operating part K^1 of the face roll K is shown formed to conform with peripheral face of the wheel when finished, with the exception that the outer corners of the tread and flange are not rounded with this roll K , 20 but such rounding will be performed by the rolling or operating part H^1 of the face roll H , as shown in Figs. 97, 98 and also illustrated in Figs. 115 and 116. Said face rolls K and H may also be operated against 25 the peripheral face of the work-piece, either together in unison, or independent of each other. In this case, said face rolls K and H are shown to be operated together in unison against the peripheral face of the work- 30 piece; that is, each roll moves the same radial distance as the other. These face rolls K and H , in this case, are forced against the peripheral face of the work-piece at diametrically opposite points while the work- 35 piece is rotating and thereby compress and enlarge the sectional area of the metal in the rim portion of new or worn wheels while the same are rolled to smaller diameter, and thus form the rim of the wheel to smaller diameter. Fig. 98 shows said new or worn car 40 wheel, shown in F^1 in Fig. 97, so rolled or formed to the form shown at F^2 , and shows the work-piece or wheel and the operating parts in their positions at the end of the rolling or operating process.

Fig. 99 shows, for instance, a work-piece or object rolled or formed, or reformed, or rerolled into a pipe flange or other article having a short central extension at one side 50 next to the forming-die and a long extension or hub formed at its other side as shown at F^2 . The forming-die W^s in this case is formed as shown with a piercer or center w^s formed integral with said forming-die 55 and has an outer diameter which, for instance, is shown the same as the outer diameter which said pipe flange or other article is to have when rolled or formed to finish, or the outer diameter of said forming-die may 60 be greater or be less than the outer diameter which said pipe flange or other article is to have when rolled or formed to finish. The die-supporting portion of the roll J^{ss} and the die-supporting portion of the roll 65 G^{ss} are shown with stepped portions, each

stepped portion having its peripheral face formed straight, or approximately so, and the side of the forming-die next to said rolls G^{ss} , J^{ss} is correspondingly shaped to fit said stepped portions of said rolls G^{ss} , J^{ss} , thereby supporting said forming-die W^s in both lateral and opposite radial directions. When said forming-die W^s with its axle E and supporting head M^{so} and the rolls G^{ss} , J^{ss} are brought into their proper positions, as 70 hereinbefore set forth, the edging roll part j^{2s} of said edging and die-supporting roll J^{ss} is against or in contact with the face roll K and the edging roll part g^{1s} of said die-supporting roll G^{ss} is against or in contact 75 with the portion H^s of the face roll H as shown, and during the operating process said parts W^s , M^{so} , G^{ss} and J^{ss} are retained 80 in the positions shown in Fig. 99. The edging and web rolling roll J^{ss} may be 85 formed similar to the edging and web rolling rolls, for instance J^1 or J^1 , &c., hereinbefore described, that is, said roll J^{ss} may be formed with a web reducing roll part j^{2s} and edging roll part j^{2s} as for instance 90 shown in Fig. 99, and said web finishing roll G^s may be formed wholly conical, and the piercer or center E^s of the supporting head M is provided with the flange or shoulder 95 e^{so} as shown. During the process of rolling 100 or forming the hub, the end face of said roll J^{ss} is in contact with the peripheral face of the flange e^{so} of said piercer or center E^s as shown and, thereby prevents the formation of any undesirable portion or fin which 105 would have to be removed afterward by turning or other costly means. Or, for instance, a piercer or center having no flange or shoulder e^{so} , as for instance E^1 in Fig. 64, may be used in place of said piercer or center E^s , and the edging and web rolling roll J^{ss} may be formed with the extension j^{2s} as 110 is shown on roll J^{ss} in Fig. 64, which extension will serve the same purpose as said flange e^{so} . During the operation of rolling 115 or forming the flange portion of the work-piece between the said portion j^{2s} of said roll J^{ss} and the forming-die W^s to its desired thickness, the edging and web rolling roll J^{ss} may be moved radially with respect 120 to the work-piece from its position shown in dotted lines adjacent the hub to the periphery of the work-piece or it may be so moved forward and backward as often as desired, and when said roll J^{ss} approaches the 125 position shown in Fig. 99, the face rolling roll K is pulled back into the position, for instance, shown and therein is not operating against the work-piece, but may be used between said edging roll portions j^{2s} , j^{2s} of said rolls J^{ss} , J^{ss} as a stop or gage to limit the lateral movement of said roll J^{ss} against the work-piece as shown and as hereinbefore described. The finishing roll G^s is then 130 moved toward and against the side of the

work-piece and operates against the side of the work-piece as shown and at the same time with the rolling or operating portion H² of the face finishing roll H, the said pipe flange or similar article is rolled or formed to the finished form or shape F² shown in Fig. 99. Said rolling or operating portion H² of said face roll H may also be used between said edging roll portion g¹²⁷ of said roll G¹¹ and the said roll G² as a stop or gage to limit the lateral movement of said roll G² against the side of the work-piece, as shown.

Fig. 100 shows, for instance, a work-piece or object rolled or formed, or reformed, or rerolled into a pipe flange or other article having a hub or central extension formed at each side, as shown at F² in Fig. 100. The forming-die W² in this case is provided with a removably fitted piercer or center E¹ and it has an outer diameter which, for instance, is shown the same as the outer diameter which said pipe flange or other article is to have when rolled or formed to finish, or the outer diameter of said forming-die may be greater or be less than the outer diameter which said pipe flange or other article is to have when rolled or formed to finish. The operating parts of the operating process are similar to the ones before described with reference to Fig. 99.

The advantages of my invention are many and will be appreciated by those skilled in the art. Some of said advantages are for instance:—

The production of car wheels and other circular objects by the use of a supporting head, a supporting axle rotatably supported on said supporting head, a piercer or center removably or exchangeably fastened to one of the ends of said supporting axle, and a forming die slidably supported on said piercer or center; the actual forming-side or forming-portion of said forming-die being shaped to conform to the form or shape of that portion of the car wheel or other body at one side thereof which reaches to a circle at the inner peripheral face of the marginal or rim portion of the wheel or other body when the same is rolled or formed to its finish; that is, the side of the work-piece next to the forming-die is pressed against the forming-die and metal of the work-piece at the side thereof next to the forming-die is forced into the forming-cavity or cavities of the forming-die inside of said circle by the action of a roll or rolls acting against the work-piece at the other side thereof. By this means, all surfaces of the work-piece or wheel, with the exception of that portion of the work-piece or wheel at one side thereof inside of said circle, are acted upon directly by rolls, and the whole rim portion with the exception of the inner peripheral face of the rim portion next to

the forming-die is rolled direct by rolls, and as soon as the metal at the peripheral face of the work-piece reaches the peripheral rolling face of the face roll K (see for instance Fig. 64 or 65), it will be rolled or worked continually until the work-piece or wheel has been rolled or formed to a desired diameter. When thus rolled, the finishing roll H operates against the peripheral face of the work-piece or wheel, whereby the metal in the whole rim portion of the work-piece or wheel is compressed or worked to its maximum and uniform density or practically so. The piercing, or penetrating, or centering and the rolling or forming of the whole car wheel or other body completely, including the dishing and the removing of the work-supporting centers, may all be done by my novel method and novel devices or means with one heat and before the work-piece or finished car wheel or other finished body is removed from the apparatus or mill; and therewith, in rolling or forming, for instance, such articles as car wheels, the metal in the flange, tread and whole rim portion of the article may be worked to maximum density where the strength of the wheel is mostly needed, thereby giving to said parts the greatest possible strength and most efficient wearing surface, thus enormously reducing the cost of operation in the manufacture or the making of car wheels or other circular articles, cheapening the product and increasing the output; or for instance, any previously formed blank or work-piece formed by any method or means into any desired form or shape such for instance as herein disclosed or similar thereto and being properly heated and having the proper volume or weight for the desired finished article, may be taken into my apparatus or mill and therewith be rolled or formed and dished or not dished, as may be desired, and finished to the desired form or shape of any of the bodies or articles as herein described or to the form or shape of any other desired article such for instance as herein disclosed, or similar thereto, and such articles may be pierced or penetrated or centered, and be rolled or formed and be dished or be not dished, as may be desired, with either the use of all the rolls or with only the use of the herein named rolls of either of the herein named finishing side or of the herein named roughing side of my novel apparatus or mill; or for instance, all the various performances required in the making of such bodies or articles as herein described from properly heated ingots, blooms, blanks or other work-pieces may either be all performed with one heat and before the work-piece or finished product is taken out of my novel apparatus or mill, or, each of such performances may be done singly or separately, as may be desired; or,

for instance, the rolling or forming of the inner peripheral faces of the marginal or rim portion of a work-piece or wheel sufficiently conical, or sufficiently inclined, as and for the purpose hereinbefore described for instance with reference to Figs. 113, 114, 116 and 117, and then rolling the metal, or part of the metal forming the so sufficiently conically rolled inner peripheral face of the rim portion of the work-piece or wheel at one side thereof into another portion of the work-piece or wheel, as and for the purpose hereinbefore described and diagrammatically illustrated with the Figs. 113 and 114; or for instance, the rolling of the total peripheral face of the work-piece or wheel, first to beaked or rudimentary form, as and for the purpose hereinbefore described with reference for instance to Figs. 66, 81, 118, 119, 120, 121, 113 and 114 and then the rolling of the so beaked rudimentarily formed peripheral face to desired finished form, as and for the purpose hereinbefore described, for instance, with reference to Figs. 118, 119, 120 and 121 and diagrammatically illustrated in Figs. 113 and 114; or for instance, such bodies or articles as herein described or any other similar desired articles which were previously finished by any process, but which were not dished, may according to my invention, be dished to any desired dish while the article revolves, and if so required, may also be rolled or formed true after the dishing is done; or, such bodies or articles as herein described or any other similar desired articles which were previously finished by any process and which were either dished or not dished and which were either bored and fitted or forced to their axles or shafts or which were not bored, may, according to my invention, be rolled or formed true, or rolled or formed to a different form or size and while such article revolves may also be dished to any desired dish or be left undished, and if bored, such bore may also be made smaller in diameter so it may again be bored to its original diameter and be again fitted to the same place on its axle or shaft; or, ingots, blooms, blanks or other work-pieces which may have been previously centered or pierced and centered and which may also have or not have the hub portion formed by any process or which may also have or not have been formed into any of the aforesaid forms or shapes by any process, may according to my invention be rolled or formed and be dished or left undished, as may be desired, to their desired form or shape; or for instance, the piercers or work-supporting centers, by constant and continuous pressure means described, also automatically clamp the hub or center portion of the work-piece firmly between them and with the forming-die revolve with the blank or work-piece while the

same is so automatically firmly clamped laterally at its hub or center portion, and during the centering or piercing or penetrating process and also during the dishing, or rolling or forming and dishing or undishing processes, said piercers or work-supporting centers with the hub or center portion of the work-piece so automatically and firmly clamped laterally between them, are moved in the direction of their axes forward or backward, such as the case may require, whereby, car wheels or other circular bodies will be rolled or formed and dished, or undished and rolled or formed, and thereby and with the aid of indicating devices or with the aid of adjustable stops, car wheels or other circular bodies will be rolled or formed and dished, &c., perfectly true, smooth and to balance and to the desired gage or gages, and when the tread and flange or peripheral face of the car wheel or other circular body being rolled reaches its desired finished diameter, said finished diameter will automatically be retained during any further rolling of the car wheel or other body, or during any further operation against said car wheel or other body; or for instance, the use of said positioning, or raising, lowering or retaining device, whereby the ingot, bloom, blank or other work-piece is brought into and retained in such position wherein its outer portion or periphery is central or coaxial, or approximately so, with the piercers or work-supporting centers to thereby permit of its being centered or pierced or penetrated in the center, or approximately in the center, of its outer portion or periphery, and after being so centered or pierced or penetrated or during said centering or piercing or penetrating process, the receiving, or positioning member of said positioning device is lowered away from the work-piece and is retained in said lowered position away from the work-piece until said work-piece or finished article is to be removed from the apparatus or mill, when the receiving or positioning member of said positioning device is again raised to receive said work-piece or finished article and remove the same from the apparatus or mill; or for instance, the use of the face roll K having its peripheral or rolling face formed as and for the purpose hereinbefore described with reference to the Figs. 118, 119, 120, 121, 113, 114 or Figs. 116 and 117 and having its lateral thickness or width the same as is the lateral thickness or width which the outer or rim portion of the car wheel or other article which is to be rolled from the work-piece is to have when finished and, the use of the edging and web rolling rolls, for instance J¹, J² or J³, &c., and the edging and die-supporting rolls for instance J⁵, J⁶ or J⁷, &c., being formed as and for the purpose

hereinbefore described for instance with reference to the Figs. 113, 114, 116 and 117 and as for instance shown in the Figs. 66, 67 or Figs. 81 and 82, &c., whereby with said roll 5 K and with said edging and web rolling rolls for instance J¹, J² or J³, &c., and with the edging and die-supporting rolls for instance J⁵⁰, J⁶⁰ or J⁶¹, &c., formed as shown and as and for the purpose hereinbefore described, the metal in the peripheral face and the whole rim portion of a car wheel or other article is also rolled or worked continually during the rolling process upon all its surfaces simultaneously with the forming-die and said three rolls formed for instance as shown and thereby, the metal in the peripheral face and the whole rim portion of a car wheel or other article is also condensed uniformly to its maximum, or practically so, 10 thus giving to said metal in said peripheral face and rim portion its due maximum and uniform strength and its due maximum and uniform resistance to wear and thereby, when the work-piece or wheel is finished 15 by my finishing rolling or forming and dishing processes to its finished form or shape, as for instance shown at F² in the Fig. 67 or 82, or by my finishing rolling or forming process to its finished form or shape, as for instance shown at F² in Figs. 77, 20 78 or 94, &c., said peripheral face and the whole rim portion is also rolled smooth on all its surfaces to the desired forms or shapes without leaving a raised circular portion or 25 fin which would have to be removed afterward by turning, or other costly means; or for instance, during the rolling or forming according to my invention, any surplus of metal in the heated work-piece may be 30 forced during the rolling or forming process to flow either into the inner peripheral portion of the rim or into the web portion adjacent the rim, or into both; or to flow into any other portion or portions of the 35 wheel or other object, without leaving a raised circular portion or fin anywhere on the finished rolled or formed wheel or other finished rolled or formed object which would have to be removed afterward by 40 turning or other costly means; or for instance, my preferred forming-die herein shown and described in some of its various forms is slidably supported on the piercer or center of the supporting head M⁵⁰ and 45 rotatable with said piercer or center, whereby with the use of the various shaped rolls, the work-piece or wheel is first rolled or formed to undished form and with said piercer or center of supporting head M⁵⁰, 50 the work-piece or wheel is dished while said forming-die together with the edging and die-supporting roll and both the face rolls H and K are retained in their positions, as 55 for instance shown in Figs. 66 and 67 and 60 as hereinbefore fully shown and described; 65 or for instance, the reworking of a new or worn car wheel, as for instance described with reference to Figs. 97 and 98; or for instance, the reworking or reforming of an object into for instance a pipe flange or 70 other circular article as for instance described with reference to Figs. 99 and 100; or for instance, the supporting head for instance M⁵⁰, fitted with the operating parts as hereinbefore described with reference to 75 Fig. 5 and Figs. 105 to 109 inclusive; or for instance, the device with reference to the Figs. 30 to 41 inclusive, for longitudinally moving the axle E with its piercer or center together with the supporting head, 80 for instance M⁵⁰, or for moving said axle E with its piercer or center independently of said supporting head M⁵⁰; said supporting head, for instance M⁵⁰, may be moved into desired position and therein retained while 85 its axle E with piercer or center may be longitudinally moved as desired; or for instance, the novel driving means and the arrangement thereof, as shown and described in my said original application, enables the 90 main driving gears and their shafts to be located below the floor and out of the way and it also enables each set of the driving rolls to be run in either direction and at various speeds relative to the other set, and 95 also that either set may be disconnected from the main driving shaft, all as fully shown and described in my said original application. Other advantages of my invention will appear from the matter hereinbefore shown and described. 100

My said preferred novel devices or means and my novel apparatus or mill wherein said devices or means are systematically arranged, as more fully shown and described 105 in my said original application, may be operated in many ways different from those herein described and still be within the scope of my invention, and it is to be understood that I do not desire to limit myself to the 110 operation of said devices or means as herein described, as such are only examples for the purpose of illustrating the manner or way by which my novel method and means for centering or piercing or penetrating 115 properly heated ingots, blooms, blanks or other work-pieces and therefrom completely rolling or forming or rolling and dishing such bodies or articles, as herein described, or other similar bodies or articles or any other 120 desired article such for instance as herein disclosed or similar thereto; or undishing, or redishing the same while the same revolves and for removing the forming-die and piercers or work-supporting centers 125 from the finished product, all may be carried out with my novel apparatus or mill.

While the apparatus or mill, in the manufacture or making of such articles as herein described, or other articles, may mostly 130

be used in rolling or forming such articles with the use of all the rolls and with the centering or piercing or penetrating and the dishing or dishing and rolling devices and 5 with the positioning, or raising, lowering and retaining device shown and more fully described in my said original application, and therewith may give best results, I do not desire to limit myself to such apparatus 10 or mill having all the rolls and the other aforesaid devices, as efficient apparatuses or mills can be made for instance with only part of such rolls, and with or without the dishing device, and with or without the 15 positioning, or raising, lowering and retaining device, as for instance described and illustrated in Figs. 5, 17 to 24, and Figs. 46, 47, 48, 49 and 61, wherewith such articles as herein described or other articles may be 20 satisfactorily made with or without the dishing; as for instance, in Figs. 17 and 18 is illustrated a car wheel which is rolled with only the use of the forming-die, for instance W¹, and the three rolls as shown; 25 that is, with the herein named edging and web rolling roll, for instance J¹, the edging and die-supporting roll, for instance J⁵⁹, and the tread or face rolling roll K and therewith the rim portion of said car wheel 30 is also supported during the dishing, or rolling and dishing process, and while the forming-die and the work-piece or car wheel revolves, it is dished to the form or shape F² in Fig. 18 in the same manner as with 35 the dishing device shown and described with reference to the Figs. 6 to 12 inclusive, and without the dishing, the car wheel would have the form or shape similar to the form F¹ in Fig. 17; or for instance, in Figs. 19 40 and 20, is illustrated a car wheel which is rolled or formed with only the use of the four rolls as shown, that is,—with the forming-die, for instance W¹, the herein named edging and web rolling roll, for instance J¹, 45 the edging and die-supporting roll, for instance J⁵⁹, the tread or face rolling roll K, and the tread or face finishing roll H, and with said forming-die W¹ and said rolls J¹, J⁵⁹ and K the rim portion of said car wheel 50 is also supported during the dishing or rolling and dishing process, and while said forming-die and the work-piece or car wheel revolves it is dished to the form or shape F² in Fig. 20 in the same manner as with 55 the dishing device shown and described with reference to the Figs. 6 to 12 inclusive, and without the dishing device, the car wheel would have a form or shape similar to the form F¹ in Fig. 19; or for instance, in 60 Figs. 21 and 22 is illustrated a car wheel which is rolled or formed from an ingot, bloom, or other work-piece having the form or shape F in Fig. 21 before being put into the apparatus or mill and therewith rolled 65 or formed with only the use of the three

rolls as shown, that is,—with the forming-die, for instance W¹, the herein named web finishing roll, for instance G¹, the die-supporting roll, for instance G¹⁴, and the tread or face finishing roll H, and therewith the rim 70 portion of said car wheel is also supported during the dishing or rolling and dishing process, and while said forming-die and the work-piece or car wheel revolves, it is dished to the form or shape F² in Fig. 22 in the 75 same manner as with the dishing device shown and described with reference to the Figs. 6 to 12 inclusive, and without the dishing device, the car wheel would have a 80 form or shape about similar to F¹ in the Fig. 19; or for instance,—in Figs. 23 and 24, is illustrated a car wheel which is rolled or formed from an ingot, bloom, or other work-piece having for instance the form or shape F in Fig. 23 before being put into 85 the apparatus or mill and therewith rolled or formed with only the use of the five rolls, as shown, that is,—with forming-die, for instance W¹, the herein named web finishing roll, for instance G¹, the die-supporting 90 roll, for instance G¹⁴, the tread or face finishing roll H, the herein named edging and web rolling roll, for instance J⁵ (which latter in this case may either be loose or driven), and the edging and die-supporting 95 roll, for instance J⁵⁹, and therewith the rim portion of said car wheel is also supported during the dishing or rolling and dishing process, and while the forming-die and work-piece or car wheel revolves it is dished 100 to the form or shape F² in Fig. 24, in the same manner as with the dishing device shown and described with reference to the Figs. 6 to 12 inclusive, and without the dishing device, the car wheel would have the 105 form or shape about similar to F¹ in Fig. 19.

It is further to be understood that I also do not desire to limit myself to pressure cylinders as herein shown and described, as efficient apparatuses or mills can be made 110 and be useful, wherein, instead of the herein shown and described double acting pressure cylinders for moving the rolls into and out of operative position with the work-piece and with their adjustable stops for limiting 115 their strokes as desired, any other form of pressure cylinder or any other suitable means may be used.

It is also further to be understood that I do not desire to limit myself, as shown for 120 instance in said Fig. 1, to the inclination or angle at which for instance the shafts J, J of said edging and web rolling roll, for instance J¹ and edging and die-supporting roll, for instance J⁵⁹, are disposed; nor the 125 diameter of the rolls for instance J¹, J⁵⁹, shown for instance in said Fig. 1. Said inclination or angle, with respect to the side of the supported work-piece or with respect to a plane at right angles with the axis of 130

- the supported work-piece, may be much greater than herein shown, or for instance the axis of one or of each of said shafts J, J, during the operating process, may be parallel or approximately parallel with the side of the supported work-piece, or for instance one shaft J may be parallel or approximately parallel with the side of the supported work-piece, while the other shaft J may be inclined to the side of the supported work-piece, all as practice may determine and depending also on the thickness and shape of the article to be rolled or formed from the work-piece, therefore the axis of such shaft or roll may be either parallel or inclined to the side of the supported work-piece and the diameter of the rolls, for instance J¹, J² or J¹, X¹, etc., may, for instance be smaller or larger, such as may be required for various purposes or as practice may determine.

Where in the specification and claims the word "coaxial" or "coaxially" is used with reference to the centering, or piercing or penetrating and centering, and to the positioning of a work-piece, &c., it is intended to mean "coaxial or approximately coaxial," &c.

Where in the specification and claims the words "ingot, bloom or blank" are used, it is intended to mean the work-piece to be operated upon, and the word "wood-piece" is used herein in a broad sense and is intended to include an ingot, bloom, blank, car wheel or any other unfinished or completely finished circular, or approximately circular object adapted to be rolled or formed, re-rolled, reworked or reformed either to entirely change its shape, or only partly change its shape or outline, or to change its dimensions in whole or part, as desired. In other words "work-piece" means any circular, or approximately circular, object to be operated upon.

Where in the specification and claims the words "sufficiently conical" or "sufficiently inclined" are used with reference to the said inner rolling or operating portion of the web reducing roll part J² of said edging and web rolling roll, for instance J¹, J¹ or J², &c., and to the inclined peripheral portion, for instance w¹ of the forming-die, for instance W¹ in Fig. 91, or with reference to the inner peripheral face or faces of the marginal or rim portion of a work-piece or wheel or other object, it is intended to mean the inclination of said inner rolling or operating portions of said web reducing roll part J² and the inclination of the peripheral portion, for instance w¹ of the forming-die, for instance W¹ in Fig. 91, being formed, &c., so as to cause the metal, during the rolling or forming of said rim portion, to flow in the proper directions to assure compression of the metal in said rim portion to uniform or to practically uniform den-

sity, as distinctly illustrated in Figs. 113, 116 and 117, and as hereinbefore fully described with reference to said Figs. 113, 116 and 117.

The foregoing description clearly sets forth various piercing or penetrating or centering and rolling or forming processes or steps and operations, according to my invention, which I prefer to employ for carrying out my invention for centering or piercing or penetrating and completely rolling or forming and dishing according to my invention, properly heated blanks or work-pieces into completely finished rolled or formed wheels or other circular bodies, in the same apparatus or mill, and while the means illustrated and described are designed to practically carry out the various steps of my invention, I do not wish to limit myself to the use of such means, as modifications thereof within the scope of the appended claims may be employed and my invention practised thereby without departing from my invention or sacrificing any of the advantages thereof.

The foregoing description and accompanying drawings further fully set forth my invention, together with portions of an apparatus or mill for carrying out my invention, and also illustrate and describe modifications in the arrangement and constructions of said portions of said apparatus or mill, which modifications may be employed for carrying out my invention, all embodying my invention. It is to be understood, however, that many modifications and changes in the construction and arrangement of the parts and in the steps and operation may still be made without departing from my invention, as defined in the claims.

The features of my invention herein described are not all claimed herein, but such features not herein claimed are covered by claims within applications filed by me and within patents issued to me and having the hereinbefore said filing dates, serial numbers and patent numbers.

I claim as my invention:—

1. In an apparatus or mill for rolling car wheels or other circular objects, a pair of oppositely arranged rotatable work-supporting means including a forming-die supported by one of said supporting means and adapted to be engaged by and rotate or assist in rotating a work-piece, and a roll or rolls acting against the work-piece to force the same against and into said die and roll the work-piece to desired form, one of said rolls being longitudinally movable and operating against the side of the work-piece opposite said forming-die.

2. In an apparatus or mill for rolling car wheels or other circular objects, combined die and roll-forging mechanism co-operat-

- ing to form a blank or other work-piece into the form of a car wheel or other circular object having a hub, a rim and a web portion, the roll-forging portion of said mechanism being adapted to roll against all exposed surfaces of the work-piece not engaged by the die-forming portion of said mechanism, including the rolling of the opposite sides and the outer peripheral face of 5 said rim.
3. In an apparatus or mill for rolling car wheels or other circular objects, a pair of work-supporting axles having piercers or centers at adjacent ends thereof between which 10 a work-piece is to be positioned, a forming-die on one of said piercers or centers and adapted to be engaged by and rotate or assist in rotating said work-piece, and rolls 15 acting against the work-piece to force the same against, into, and over the edge of said die and to roll the work-piece to desired undished form, and means including said axles for dishing the work-piece while 20 rotating or leaving the same in undished form.
4. In rolling mechanism, a rotatably supported forming-die against which one side of a work-piece is adapted to be forced, rolling means for rolling the work-piece 25 against and into said forming-die and over the peripheral edge thereof and for rolling the exposed portions of the work-piece to desired form, including the rolling of the opposite sides and the outer peripheral face of 30 a flanged rim or marginal portion.
5. In rolling mechanism for rolling a car wheel or other similar circular object, the combination of a forming-die rotatably supported, and rolls adapted to act against 35 the work-piece to force the same against and into the forming part or parts of said forming-die and over the peripheral edge of the forming-die to form one side of the work-piece or car wheel or other object to 40 the shape of said die and to roll the work-piece as desired on all of its surfaces out of contact with said forming-die, including the rolling of the opposite sides and the outer 45 peripheral face of the rim of the work-piece.
6. In rolling mechanism, rotatable work-supporting means including a pair of aligned 50 rotatable axles having means or being formed at adjacent ends thereof to engage a work-piece and between which means or 55 formed ends the work-piece is adapted to be positioned, a forming-die carried by one of said axles, and rolls adapted to roll in contact with said work-piece to cause the same to be shaped at one side to the shape of said 60 die and to roll the remaining surfaces of the work-piece to desired form, including the rolling of the outer peripheral face of the work-piece.
7. In rolling mechanism, combined die and 65 roll-forging means for forming a car wheel
- having a flanged rim portion, the roll-forging portion of said means being so arranged relative to the die-forging portion thereof to roll the entire rim portion and one side of that portion of the work-piece surrounded by said rim portion and to cause said portion of the work-piece at the other side thereof to be formed to the shape of said die-forging portion. 70
8. In an apparatus or mill of the kind described, rotatable work-supporting means, and combined die and roll-forging mechanism, the die-forging portion of said mechanism being supported by said work-supporting means and the roll-forging portion of 75 said mechanism being so arranged relative to the die-forging portion thereof to roll the entire rim portion and one side of that portion of the work-piece surrounded by said rim portion and to cause said portion of the work-piece at the other side thereof to be formed to the shape of said die-forging portion. 80
9. In rolling mechanism, a pair of aligned work-supporting axles rotatably supported 85 and adapted to support a work-piece therebetween, a forming die supported by one of said axles and adapted to be engaged by one side of the work-piece, a roll for acting against the other side of the work-piece to 90 cause said one side thereof to be formed to the shape of said forming-die and to cause the work-piece to be enlarged in diameter so as to cause its marginal portion to extend beyond the periphery of the inner rim 95 face forming portion of said forming die, said roll being also adapted to roll said other side of the work-piece to desired shape, and rolls coacting with said roll to roll the opposite sides and the outer peripheral face 100 of the extending marginal portion of the work-piece to desired shape. 105
10. In an apparatus or mill for rolling or forming car wheels or other circular objects, a pair of aligned work-supporting axles rotatably supported and having detachable piercers or centers secured to adjacent ends thereof to support a work-piece therebetween, a forming die supported on one of said piercers or centers, and rolling mechanism for causing the work-piece at one side thereof to be formed to the shape of said forming-die and to roll the remainder of the work-piece to desired shape. 110
11. In an apparatus or mill of the kind 115 described, aligned work-supporting axles arranged at opposite sides of a work-piece and having piercers or centers secured to adjacent ends thereof adapted to pierce or penetrate and support or partly support a work-piece therebetween, said piercers or centers having piercing portions and opposing shoulders of larger diameter than said piercing portions to gage the length of the hub to be formed, a forming die supported 120
- 125
- 130

- by one of said piercers, and rolling mechanism for causing the work-piece at one side thereof to be formed to the shape of said forming-die and for rolling or forming 5 metal at said side around one of said piercers and against the shoulder thereof, for rolling metal at the other side of the work-piece around the other piercer and against the shoulder thereof and for rolling 10 the remaining surfaces of the work-piece including the rolling of the opposite sides and the outer peripheral face of the rim portion to desired shape.
12. In an apparatus or mill of the kind 15 described, a pair of aligned work-supporting axles arranged at opposite sides of a work-piece and having piercers or centers secured to adjacent ends thereof provided with piercing or centering portions and opposing 20 shoulders of larger diameter than said piercing or centering portions to limit the extent of penetration of said piercers into the work-piece, a forming die supported by one of said piercers and arranged at one side 25 of the work-piece, a side roll at the other side of the work-piece adapted to roll the work-piece against said forming-die to cause the first-mentioned side thereof to be formed to the shape of said die and to roll 30 said other side to desired shape, and a peripheral face roll coacting with said side roll to cause the peripheral face and one side of the marginal portion of the work-piece to be rolled to desired shape.
13. In rolling mechanism, a forming-die 35 against which one side of a work-piece is adapted to be forced, a side roll adapted for rolling against the other side of the work-piece to cause the first-mentioned side thereof to be shaped to the form of said die and 40 to cause the work-piece to be extended radially beyond the peripheral edge of said die, a peripheral face roll coacting with said side roll to cause the peripheral face of the 45 extended marginal portion of the work-piece to be rolled to desired form, and a roll for supporting and rotating said forming-die and for rolling against the side of the extended marginal portion of the work-piece at said first mentioned side of the 50 work-piece.
14. In rolling mechanism, a forming-die against which one side of a work-piece is adapted to be forced, opposite side rolls 55 and a face roll against opposite sides of which said side rolls rotate, one of said side rolls serving to rotate said forming-die and the other acting to roll in contact with the work-piece to cause one side thereof to 60 be formed to the shape of said forming-die and to roll the other side thereof to desired shape and cause the marginal portion of the work-piece to be extended beyond and be forced over the peripheral edge of said 65 forming-die, said first-mentioned side roll being also adapted to roll against or in contact with the side of the extended marginal portion of the work-piece at the first-mentioned side thereof and coacting with said second-mentioned side roll and with said 70 face roll to roll the marginal or rim portion of the work-piece to desired shape.
15. In rolling mechanism, a forming-die adapted to impart the desired shape to one side of a work-piece, and rolls acting against 75 all surfaces of the work-piece out of contact with said die, at least one of said rolls serving to roll the work-piece against and into said forming-die and beyond the peripheral edge thereof to permit the remaining rolls 80 to act against the marginal or extended marginal portion of the work-piece for rolling said marginal portion to desired lateral thickness and the outer peripheral face thereof to desired shape. 85
16. In an apparatus or mill for rolling or forming car-wheels or other circular objects, a pair of aligned and longitudinally movable work-supporting elements between which a work-piece is to be positioned, a forming-die supported by one of said work-supporting elements and adapted to be engaged by and rotate or assist in rotating said work-piece, a side roll or rolls adapted to force said work-piece against said die to 90 cause one side of said work-piece to be formed to the shape of said die and to roll the other side of the work-piece to desired shape, and rolls coacting with said side roll or rolls for rolling the marginal portion of 95 the work-piece to desired lateral thickness and the outer peripheral face thereof to desired shape. 100
17. In an apparatus or mill for rolling or forming car wheels or other circular objects, 105 rotatable work-supporting means between which a work-piece is to be positioned, a forming-die supported by a part of said supporting means and adapted to be engaged by and rotate or assist in rotating said work-piece, a side roll adapted to force said work-piece against said die to cause one side thereof to be formed to the shape of said die and to roll the other side of the work-piece to desired shape, and a pair of rolls coacting 110 with said side roll for rolling the opposite sides and the outer peripheral face of the marginal or rim portion of the work-piece to desired shape, one roll of said pair of rolls being also adapted to rotate or assist in 115 rotating said forming-die and said side roll being also adapted to rotate or assist in rotating said work-piece. 120
18. In an apparatus or mill for rolling or forming car wheels or other circular objects, 125 a pair of aligned work-supporting axles between which a work-piece is to be supported, a forming-die at one side of the work-piece of smaller diameter than the article to be rolled is to be when finished, 130

a side roll at the other side of the work-piece adapted to force the work-piece against said die to cause the work-piece at the first-mentioned side thereof to be formed 5 to the shape of said die and to roll said other side of the work-piece to desired shape and cause metal of the work-piece to be extended radially beyond the peripheral edge of said die, a second side roll at said first- 10 mentioned side of the work-piece to roll the side of the extended or marginal portion of the work-piece, and a peripheral face roll positioned between said side rolls and having a portion of its opposite sides in contact 15 with said side rolls, and said side rolls and said peripheral face roll being adapted to roll the opposite sides and the outer peripheral face of the extended or marginal portion of the work-piece to desired shape and 20 the metal of said marginal portion to uniform density or practically so, substantially as described.

19. In an apparatus or mill for rolling or forming car-wheels or other circular objects, a rotatably supported forming-die against or into or over which a work-piece is adapted to be rolled, and a die-supporting and edge rolling roll having a die-supporting portion adapted to roll in contact with 30 the outer side of said die and having an edge rolling portion in contact with the peripheral edge of said die, said edge rolling portion extending outwardly from said peripheral edge and being adapted to roll against or in contact with the side of the 35 marginal or rim portion of the work-piece extending outwardly from the peripheral edge of said die.

20. In rolling mechanism, a rotatably supported forming-die and a roll coöperating with said die and between which roll and die a work-piece is adapted to be positioned, means for rotating and applying rolling pressure to said roll to cause the side of the 40 work-piece engaged by said die to be formed to desired shape by said die, and rolls coöperating with said roll, all of said rolls being adapted to act and roll all exposed surfaces of the work-piece to desired shape including the rolling of the opposite sides and the outer peripheral face of the marginal or rim portion of the work-piece.

21. An apparatus or mill for rolling or forming car wheels or other circular objects, having means to engage and pierce or penetrate a work-piece at opposite sides thereof at the center of its outer portion or periphery and to rotatably support the same at its central portion, a forming-die at one 45 side of said work-piece and extending to the inner peripheral face of the rim of the work-piece or of the completed article, and rolls rolling against all exposed surfaces of the work-piece, including rolling against the 50 opposite sides and the outer peripheral face

of the marginal or rim portion of the work-piece, at least one of said rolls causing the work-piece to be formed to the shape of said forming-die.

22. In rolling mechanism of the kind described, the combination of means arranged at opposite sides of a work-piece for centrally piercing or penetrating or centering and supporting the work-piece from opposite sides thereof and having suitably formed piercers or centers provided with piercing or centering portions and with circumferential flanges or shoulders of larger diameter than said piercing or centering portions, said flanges or shoulders being 70 adapted to be spaced from opposite sides of the supported work-piece to limit or govern the length which the hub of the work-piece or finished object is to have, a forming-die carried by one of said piercers or centers and 75 having a hub-forming cavity, a combined die-supporting and edge rolling roll coacting with said forming-die and adapted to support the same and to roll the side of the marginal or rim portion of the work-piece 80 at the side thereof engaged by said forming-die, a longitudinally and also laterally movable edging and web rolling roll adapted to roll against and into the other side of the work-piece to forcibly press the work-piece 85 against said forming-die and into the hub-forming cavity thereof and also against the flange or shoulder of the piercer or center carrying said forming-die, for imparting the shape of said die to the side of the work-piece engaged by said die, for reducing the thickness of the work-piece within a circular region between its marginal portion and its center or hub portion and for causing 90 metal of the work-piece to flow toward the axis or hub portion of the work-piece and laterally against the flange or shoulder of the piercer or center at said other side of the work-piece.

23. In rolling mechanism of the kind described, two coöoperating members, one a forming-die arranged at one side of the work-piece and having its peripheral edge adapted to determine the location of and form the inner peripheral face of the rim of 110 said work-piece or the rim of the completed article, and the other a rolling member arranged at the opposite side of the work-piece and adapted to roll said work-piece against said forming die to form said first- 115 mentioned side of the work-piece to the shape of said forming-die and to roll said opposite side including the rolling of the hub portion thereof and the side of the marginal or rim portion thereof to desired 120 form.

24. In rolling mechanism, three coöperating members adapted to roll or form car-wheels or other circular articles having each a hub, a web and a rim, one a forming-die 125

arranged at one side of a work-piece and having its peripheral edge adapted to determine the location of and form the inner peripheral face of the rim of said work-piece or of the rim of the car wheel or other article when completed, the second a rolling member arranged at the other side of the work-piece and adapted to roll said work-piece against said forming-die to form said first-mentioned side of the work-piece to the shape of said forming-die and to roll said other side of the work-piece including the rolling of the hub portion thereof and the side of the rim portion thereof to desired form, and the 5 third a face roll for rolling the peripheral face of the work-piece.

25. In an apparatus or mill of the kind described, the combination of means for centrally piercing or penetrating or centering and supporting a work-piece having a suitably formed piercer or center at one side of the work-piece provided with a piercing or centering portion and a circumferential flange or shoulder of larger diameter than said piercing or centering portion, said flange or shoulder being adapted to be spaced from said side of the supported work-piece, a forming-die at the other side of the work-piece having a central hub-forming cavity, a roll adapted to roll against the first-mentioned side of the work-piece and to move from the marginal or peripheral portion toward the center or hub portion of the work-piece to force the work-piece against said forming-die and cause metal of the work-piece to enter said hub-forming cavity and also cause said other or die-side of the work-piece to be otherwise formed to the shape of said forming-die, 40 said roll being also adapted to reduce the thickness of the work-piece within a circular region between its marginal portion and its center or hub portion and to cause metal of the work-piece to flow toward the axis 45 or hub portion of the work-piece and laterally against the flange or shoulder of said piercer or center at said first-mentioned side of the work-piece.

26. In an apparatus or mill for rolling or 50 forming car wheels or other circular objects, means for centrally and rotatably supporting a work-piece, a forming-die at one side of the work-piece adapted to form said side of the work-piece from its rim inwardly 55 only, and means for rolling all remaining exposed surfaces of the work-piece including the rolling of the outer peripheral face thereof.

27. In an apparatus or mill for rolling or 60 forming car wheels or other circular objects, combined die and roll-forging mechanism cooperating to form a blank or other work-piece into the form of a car wheel or similar article having a hub, a web, and a 5 rim, and means for centrally and rotatably

supporting said work-piece, said mechanism comprising a forming-die having a central hub forming cavity and an inclined peripheral forming-edge, said forming-die being positioned at one side of the work-piece, a 70 roll or rolls adapted to act against the other side of the work-piece to force metal of the work-piece against and into said forming-die and over and against said inclined peripheral edge and to roll said other side of 75 the work-piece to desired shape, rolls adapted to act against the peripheral face of the work-piece and roll said face first to rudimentary form and then to finished form, and means for axially moving said supporting means independent of said forming-die and said rolls to dish the work-piece.

28. In an apparatus or mill for rolling or forming car-wheels or other circular objects, a pair of work-supporting axles between 85 which a work-piece is to be positioned, a forming-die at one side of the work-piece and carried by one of said axles and having a central hub-forming cavity and a peripheral forming-edge, a roll at the other side 90 of the work-piece adapted to act against said side and roll metal of the work-piece into said cavity and over the peripheral forming-edge of said forming-die, said roll acting also to roll said 95 other side of the work-piece to desired shape, a combined die-supporting and edge rolling roll adapted to support said forming-die and to roll against the side of the metal rolled over the peripheral forming-edge of said 100 forming-die by said first-mentioned roll, and a face roll between said rolls adapted to roll the peripheral face of the work-piece.

29. In an apparatus or mill for rolling or forming car wheels or other circular objects, 105 a pair of aligned axles having piercers or centers at adjacent ends thereof between which a work-piece is adapted to be positioned, a forming-die at one side of the work-piece carried by one of said axles and having a 110 circular groove or track in its outer side, a rolling roll having a portion thereof entering said track and a portion thereof adapted to roll the side of the marginal or rim portion of the work-piece outwardly from the 115 peripheral edge of said forming-die, a rolling roll at the other side of the work-piece adapted to force the work-piece against said forming-die and over the peripheral edge thereof and to roll said other side of the 120 work-piece to the form of a hub portion, a rim portion, and a reduced or web portion, said rolls acting in conjunction with or in opposition to each other to condense the metal in said rim portion, and a peripheral 125 face roll between said rolls acting against the peripheral face of the work-piece to form the same to desired shape and to assist in condensing the metal in said rim portion.

30. In an apparatus or mill for rolling or 130

- forming car-wheels or other circular objects, a rotatable forming-die having a forming-side or forming-face adapted to be engaged by one side of a work-piece and having a 5 circular groove or track at its other side, and a die-supporting and edge rolling roll having a portion thereof entering said groove or track to operate in contact therewith and a portion of said roll extending outwardly 10 from the peripheral edge of said die and adapted to roll against or in contact with the side of the portion of the work-piece extending outwardly from the peripheral edge of said die.
- 15 31. In an apparatus or mill for rolling or forming car wheels or other circular objects, a pair of work-supporting axles having means at adjacent ends thereof adapted to centrally engage, pierce, or penetrate a 20 work-piece, a forming-die supported by one of said axles and being coaxial therewith, a roll or rolls at the side of said work-piece out of contact with said forming-die adapted to cause the work-piece at the 25 other side thereof to be formed to the shape of said die and to cause the work-piece at said first mentioned side thereof to be rolled to desired form or shape, and means for moving said axles together longitudinally independent of said forming-die to dish the work-piece to desired form.
32. In an apparatus or mill for rolling or forming car wheels or other circular objects, a pair of work-supporting axles having 35 means at adjacent ends thereof adapted to centrally engage, pierce, or penetrate a work-piece at opposite sides thereof, an edging and web rolling roll operating against one side of the work-piece, an edging roll at 40 the other side thereof, a face roll to roll the peripheral face of the work-piece, a forming-die at said other side of the work-piece against which the work-piece is forced by said edging and web rolling roll, and means 45 for moving said work-supporting axles together longitudinally independent of said forming-die and said rolls.
33. In an apparatus or mill for rolling or forming car wheels or other circular objects, a pair of work-supporting axles having 50 means at adjacent ends thereof adapted to centrally engage a work-piece, combined die and roll-forging mechanism for forming or rolling said work-piece to desired 55 shape, and means for moving said work-supporting axles together longitudinally to dish said work-piece.
34. In an apparatus or mill for rolling or forming car wheels or other circular objects, a pair of work-supporting axles having 60 means at adjacent ends thereof adapted to centrally engage a work-piece, combined die and roll-forging mechanism for forming or rolling said work-piece to desired 65 shape, said mechanism including a forming-die arranged at one side of the work-piece, and means for moving said work-supporting axles and forming-die together in one direction.
35. In an apparatus or mill for rolling or 70 forming car wheels or other circular objects, a pair of rotatable work-supporting axles having means at adjacent ends thereof adapted to centrally support a work-piece, a forming-die supported by one of said axles, a roll or 75 rolls adapted to rotate and press the work-piece against said forming-die and thus shape opposite sides of the work-piece to desired form, and means for moving said roll or rolls and die together while retaining 80 said work-supporting axles in fixed rotatable position.
36. In an apparatus or mill for rolling or forming car wheels or other circular objects, a pair of aligned supporting heads arranged 85 at opposite sides of the work-piece and longitudinally movable toward and from each other or together in one direction, a pair of aligned piercing or work-supporting axles rotatably supported by said supporting heads, independently acting power or pressure means operatively connected to said supporting heads for moving the same, a forming-die supported by one of said work-supporting axles and adapted to have 90 one side of the work-piece forced thereagainst, a roll or rolls acting against the opposite side of the work-piece to force the latter against said forming-die and to roll 95 said opposite side of the work-piece to desired shape, and means for causing said axles to be moved independent of said supporting heads or with the same.
37. In an apparatus or mill for rolling or forming car-wheels or other circular objects, 100 a pair of aligned rotatable work-supporting axles having means at adjacent ends thereof adapted to centrally engage a work-piece, a forming-die supported by one of said axles, a pair of combined die-supporting and edge 105 rolling rolls engaging said forming-die at opposite sides of its axis, said rolls having their die-supporting portions rolling in contact with said die and their edge rolling portions extending outwardly from the peripheral edge of said die, a side roll at the exposed side of the work-piece and adapted to force the other or die-side of the work-piece against said die to impart the form 110 thereof to said other or die-side of the work-piece and to roll metal at said exposed side of the work-piece toward the axis thereof and also to force metal of the work-piece 115 over the peripheral edge of said die and against at least the edge rolling portion of one of said combined die-supporting and edge rolling rolls, and a peripheral face roll between said last-mentioned edge rolling portion and said side roll with a portion of 120 its opposite sides in contact with the pe- 130

ripheral faces of said edge rolling portion and said side roll, said peripheral face roll being adapted to roll the peripheral face of the work-piece to desired form.

- 5 38. In an apparatus or mill for rolling or forming car wheels or other circular objects, a pair of rotatable work-supporting axles, having means at adjacent ends thereof adapted to centrally support a work-piece, 10 a forming-die carried by one of said axles, a combined die-supporting and edge rolling roll having a loose part in contact with said forming-die and having its other part adapted to roll one side of the rim portion 15 of the work-piece, an edging and web rolling roll at the other side of the work-piece adapted to force the latter against said forming-die to impart to the work-piece the form of said die, said edging and web rolling roll also acting to roll said other side of the work-piece to desired form, and a face roll adapted to roll against the peripheral face of the work-piece. 20
39. In an apparatus or mill for rolling or forming car wheels or other circular objects, 25 the combination of a forming-die having its inner side or forming face serving as forming surfaces and having its outer side stepped to provide contact faces in different planes, a stepped die-supporting roll of diminishing size toward its outer end in contact with the stepped outer side of said die, and a side roll or rolls between which and said forming-die a work-piece is adapted 30 to be placed, said side roll or rolls acting to force the work-piece against said forming-die and to roll the surfaces engaged thereby to desired form. 35
40. In an apparatus or mill for rolling or forming car-wheels or other circular objects, 40 the combination of a forming-die whose outer diameter is the same or less or greater than the diameter which the car-wheel or other object is to have, rolling rolls coacting with said forming-die to roll or form a work-piece, including the rolling of its peripheral face to desired shape, and means engaging the marginal portion of said forming-die for supporting said forming-die and 45 resisting both lateral and opposite radial movements thereof. 50
41. In an apparatus or mill for rolling or forming car wheels or other circular objects, means for centrally and rotatably supporting a work-piece, a forming-die at one side 55 of the work-piece having its outer face stepped, a substantially conical stepped die-supporting roll engaging the stepped portion of said forming-die, and rolls coacting with said forming-die to form the work-piece to desired shape. 60
42. In an apparatus or mill for rolling or forming car wheels or other circular objects, a pair of aligned longitudinally movable 65 work-supporting members between adjacent
- ends of which a work-piece is adapted to be positioned, a forming-die at one side of the work-piece carried by one of said members, means for moving said members longitudinally to form a rudimentary bore or part 70 or parts thereof in said work-piece, and a rolling roll or rolls at the other side of said work-piece adapted to roll the latter against said forming-die and also to roll said other side of the work-piece to desired shape. 75
43. In an apparatus or mill for rolling or forming car-wheels or other circular objects, a longitudinally movable work-supporting member at one side of a work-piece and at one end of which member the work-piece is 80 to be positioned centrally, a forming-die at the other side of the work-piece, means for moving said work-supporting member to form a rudimentary bore or a part thereof axially in said work-piece, and a rolling roll 85 or rolls at said first-mentioned side of the work-piece adapted to force the work-piece against said die and to cause said die-side of the work-piece to be formed to desired shape by said die and also to roll the side 90 of the work-piece engaged by said rolling roll to desired shape, said work-supporting member being movable independently of said rolling roll. 95
44. In an apparatus or mill for rolling or forming car-wheels or other circular objects, a longitudinally movable rotatable work-supporting member at one side of a work-piece, a forming-die at the other side of the work-piece, said forming-die being of a 100 diameter to reach only to the inner peripheral face of the rim of the car-wheel or other object when finished, said work-supporting member being adapted to center the work-piece or form an axial rudimentary bore or 105 a part thereof in said work-piece, a side roll at said first-mentioned side of the work-piece adapted to force the work-piece against said forming-die and cause said other or the die-side of the work-piece to be 110 formed to desired shape by said die and also extend the work-piece radially to reach over and beyond the peripheral edge of said die, and rolling rolls coacting with said side roll to roll the opposite sides and the outer 115 peripheral face of the extended marginal or rim portion of the work-piece as desired. 120
45. In an apparatus or mill for rolling or forming car wheels or other circular objects, a longitudinally movable work-supporting member, a forming-die between which and said work-supporting member a work-piece is adapted to be positioned so as to be rolled or formed into the form of a car wheel or other object having a hub, a web, and a rim, 125 the outer diameter of said forming-die reaches only to the inner peripheral face of the rim of the car wheel or other object when finished, and rolls co-operating with each other and at least in part with said 130

forming-die to roll all exposed portions of the work-piece not engaged by said forming-die including the rolling of the opposite sides and the outer peripheral face of said 5 rim to desired form and the whole rim portion to uniform density or practically so, substantially as described.

46. In an apparatus or mill for rolling or forming car wheels or other circular objects, 10 a pair of aligned rotatable work-supporting axles having means or being formed at adjacent ends thereof to engage a work-piece and between which means or ends a work-piece is adapted to be positioned, a forming-die carried by one of said axles and coaxial therewith, and rolls coöperating with each 15 other and with said forming-die to roll the outer peripheral face and all other portions of the work-piece not engaged by said axles 20 and said die to desired form.

47. In an apparatus or mill for rolling or forming car-wheels or other circular objects, a pair of aligned rotatable work-supporting axles having means or being formed 25 at adjacent ends thereof to engage a work-piece and between which means or ends the work-piece is adapted to be positioned, a forming-die carried by one of said axles and having a central hub forming cavity, means 30 for moving the other axle lengthwise to form an axial rudimentary bore or a part thereof in said work-piece, and rolls co-operating with each other and with said forming-die to roll the peripheral face and 35 all other portions of the work-piece not engaged by the means or ends of said axles and by said die to desired form, one of said rolls acting also to force metal of the work-piece into said hub forming cavity.

48. In an apparatus or mill for rolling or forming car wheels or other circular objects, a pair of aligned work-supporting axles having centers or piercers at adjacent ends between which a work-piece is adapted to be 45 positioned, a forming-die having a central bore into which the center or piercer of one of said axles is adapted to fit and having also a central hub forming cavity around said center or piercer, means for moving the 50 other axle longitudinally to cause the center or piercer thereof to enter the work-piece, a peripheral face roll adapted to operate against the peripheral face of said work-piece, a side roll or rolls adapted to act 55 against the work-piece at the side thereof out of engagement with said forming-die to force metal of the work-piece into said cavity and around the center or piercer surrounded by said cavity and to roll metal 60 of the work-piece onto and over the peripheral edge of said die and against said peripheral face roll, said side roll or rolls being also adapted to roll the side of the work-piece engaged thereby to desired form.

49. In an apparatus or mill for rolling or

forming car wheels, or other circular objects, a work-supporting axle having a center or piercer, a forming-die between which and said center or piercer a work-piece is adapted to be positioned to be rolled or formed into a car-wheel or other circular object having a rim portion, a face roll adapted to operate against the peripheral face of the work-piece, a pair of opposite side rolls, one of said side rolls being arranged at the side of the work-piece not engaged by said forming-die and being adapted to force the work-piece against said forming-die and cause the other side of the work-piece to be formed to desired shape by 80 said forming-die and also to extend metal of the work-piece radially over and beyond the peripheral edge of said die, the extended portion of the metal of the work-piece being adapted to be rolled at opposite sides by 85 said pair of side rolls, said side rolls having portions thereof extending across and beyond the opposite sides of said extended portion of the metal and also over and against portions of the opposite sides of the 90 marginal portion of said peripheral face roll, said peripheral face roll having at its marginal portion a total lateral thickness or total width which determines the final width of the marginal or rim portion of the work-piece, said side rolls and said face roll being formed and coacting to roll the metal in the whole rim portion to uniform or to practically uniform density, substantially as described, and said side roll at the side of the 100 work-piece not engaged by said die being also adapted to roll said side of the work-piece not engaged by said die to desired shape from the marginal or rim portion inwardly.

50. In an apparatus or mill for rolling or forming car-wheels or other circular objects, a pair of aligned rotatable work-supporting axles having means or being formed at adjacent ends thereof to engage a work-piece and between which means or ends a work-piece is adapted to be positioned, a forming-die adapted to engage one side of the work-piece and being supported by one of said axles, said forming-die having a 110 central hub-forming cavity and a web forming-portion inclined to a plane at right angles to the axis of the forming die and having an inner-rim-face forming portion at an angle with said web forming-portion, a combined die-supporting and edging roll in contact with said forming-die and having its edging roll part against and extending outwardly from the peripheral edge of said forming-die, the axle at the side of the work-piece not engaged by said forming-die being adapted to be moved longitudinally to force metal of the work-piece into said hub forming cavity by means of said engaging means or end of said axle, and an edging and 120 125 130

web rolling roll at said side of the work-piece not engaged by said forming-die adapted to force metal of the work-piece into said cavity and to force the work-piece 5 against the web forming portion and over and against the inner-rim-face forming portion of said die and also to extend metal of the work-piece radially beyond the peripheral edge of said forming-die, said edging and web rolling roll being also adapted 10 to roll the side of the work-piece engaged thereby to desired form or shape, and a peripheral face roll adapted to act against the peripheral face of the work-piece and roll the same to desired shape, said face roll having at its marginal portion a total lateral thickness or total width which is the same as the lateral thickness or width which the rim or marginal portion of the work-piece is 15 20 to have when finished, said combined die-supporting and edging roll and said edging and web rolling roll being also adapted to roll in contact with or against the opposite sides of the rim or marginal portion of the work-piece and to roll in contact with the opposite sides of the marginal portion of said peripheral face roll, said combined die-supporting and edging roll and said edging and web rolling roll and said peripheral face 25 30 35 roll being formed and coacting to govern the lateral thickness of said rim or marginal portion and to roll the metal in the entire rim or marginal portion to uniform or practically uniform density, substantially as described.

51. In an apparatus or mill for rolling or forming car-wheels or other circular objects, a pair of alined rotatable work-supporting axles having means or being formed at adjacent ends thereof to engage a work-piece and between which means or ends a work-piece is adapted to be positioned, a forming-die engaging one side of the work-piece and supported by one of said axles, said forming-die having a central hub forming cavity and a web forming portion inclined to a plane at right angles to the axis of the forming-die and having an inner-rim-face forming portion at an angle with said web forming portion, combined die-supporting and edging rolls in contact with said forming-die and each having its edging roll part against and extending outwardly from the peripheral edge of said forming-die, an edging and web rolling roll adapted to act 40 45 50 55 60 65 against the work-piece at the side thereof not engaged by said forming-die and adapted to force metal of the work-piece into said hub forming cavity so as to form the hub portion at the side of the work-piece engaged by said die, said edging and web rolling roll with the engaging means or end of one of said axles being also adapted to form the hub portion at the side of the work-piece not engaged by said die and said

edging and web rolling roll being also adapted to force the work-piece against the web forming portion of said forming-die and to force metal of the work-piece outwardly over and against the inner-rim-face forming portion of said die and beyond the same and to roll the inner peripheral face of the rim of the work-piece at the side thereof not engaged by said die, a peripheral face roll coacting with said edging and web rolling roll and with one of said combined die-supporting and edging rolls to roll the rim portion of the work-piece to desired lateral thickness and the outer peripheral face of said rim to desired rudimentary form, a web finishing roll and a peripheral face finishing roll co-operating with the other of said combined die-supporting and edging rolls at another point of said rim to roll the inner peripheral face of said rim and adjacent web portion of the work-piece at the side thereof not engaged by said die and the outer peripheral face of said rim to finished form.

52. In an apparatus or mill for rolling or forming car-wheels or other circular objects, the combination of a pair of alined axles having piercers or work-supporting centers at adjacent ends for supporting a workpiece to permit its being rotated, a pair of side rolls at opposite sides of the work-piece positioned in a plane passing laterally through the work-piece at one side of a plane passing centrally through the work-piece, one of said rolls being laterally movable against and away from the work-piece and being longitudinally movable between the center portion and the marginal portion or periphery of the work-piece, a forming-die against which the work-piece is forced by said last-mentioned roll and which forming-die is also rotatably supported by the other roll, said other roll being adapted to act against the side of the rim portion of the work-piece at the side thereof engaged by said forming-die and said first-mentioned roll being adapted to act against the other side of the work-piece from its hub outwardly toward the periphery thereof, or vice versa, a peripheral face roll adapted to act against the peripheral face of the work-piece and being positioned between said pair of side rolls, means for positively rotating at least one of said side rolls, and means for moving said alined axles together in one direction to dish or undish the workpiece or car wheel or other object while the same is rotated by said positively rotated side roll or rolls and its marginal or peripheral portion laterally supported and retained by means of said forming-die and said side rolls.

53. In an apparatus or mill for rolling or forming car-wheels or other circular objects, rotatable work-supporting centers for

56. piercing or penetrating and supporting a work-piece, a power or pressure device co-operating with each of said work-supporting centers, a rod for each of said power or pressure devices provided with a threaded portion, a removable distance sleeve secured to and slidable on each of said rods, an adjustable nut threaded onto the threaded portion of each of said rods and bearing 10 against said sleeve and together with said sleeve being adapted to engage a stationary portion of said power or pressure device to govern the longitudinal or axial movement of its co-operating work-supporting center away from the work-piece or with the work-piece, one of said sleeves or each of said sleeves being provided with one or more members or sections adapted to be moved into and out of operative position with the stationary portion of said power or pressure device.
57. In an apparatus or mill for rolling or forming car wheels or other circular objects, alined work-supporting means for supporting a work-piece therebetween, longitudinally movable rods to each of which one of said work-supporting means is operatively connected, a stop sleeve secured to one or to each of said rods and having a swinging member adapted to be moved against 75 or away from one end of said sleeve so that said sleeve or said swinging member may engage a fixed portion of the apparatus to govern the extent of longitudinal or axial movement of the co-operating work-supporting means in one direction.
58. In an apparatus or mill for rolling or forming car wheels or other circular objects, alined piercers or work-supporting centers for supporting a work-piece therebetween, longitudinally movable rods to each of which one of said piercers or centers is operatively connected, each rod having a threaded portion, a sleeve secured to each of said threaded portions and provided with a laterally extending arm, a swinging member secured to said arm and being adapted to be moved against or away from one end of said sleeve to govern the longitudinal or axial movement of the co-operating piercers or 90 work-supporting center away from the work-piece or with the same.
59. In an apparatus or mill for rolling or forming car wheels or other circular objects, a pair of longitudinally movable members to each of which one of said piercers or centers is secured, a stop-sleeve secured to one or to each of said members and having a movable portion adapted to be moved into or out of engaging position with a stationary portion of the apparatus to govern the longitudinal or axial movement of its co-operating piercer or work-supporting center away from the work-piece or with the same.
60. In an apparatus or mill for rolling or forming car wheels or other circular objects, alined piercers or work-supporting centers for supporting a work-piece there- 105 between, a pair of longitudinally movable rods to each of which one of said piercers or centers is attached, a stop-sleeve detachably secured to each rod and being of a given length to stop the longitudinal movement of said rod in one direction after traveling a predetermined distance, a stop-sleeve adapted to be substituted for said first-mentioned stop-sleeve and being of less length than the latter, said second-mentioned stop-
61. sleeve having a movable member adapted 65 to be moved into or out of engagement with a fixed portion of the apparatus to govern the extent of longitudinal or axial movement of the co-operating piercer or work-supporting center away from the work-piece or with the same.
62. In an apparatus or mill for rolling or forming car wheels or other circular objects, alined piercers or work-supporting centers for supporting a work-piece therebetween, longitudinally movable rods to each of which one of said piercers or centers is operatively connected, a stop sleeve secured to one or to each of said rods and having a swinging member adapted to be moved against 80 or away from one end of said sleeve so that said sleeve or said swinging member may engage a fixed portion of the apparatus to govern the extent of longitudinal or axial movement of the co-operating work-supporting means in one direction.
63. In an apparatus or mill for rolling or forming car wheels or other circular objects, alined piercers or work-supporting centers for supporting a work-piece therebetween, longitudinally movable rods to each of which one of said piercers or centers is operatively connected, each rod having a threaded portion, a sleeve secured to each of said threaded portions and provided with a laterally extending arm, a swinging member secured to said arm and being adapted to be moved against or away from one end of said sleeve to govern the longitudinal or axial movement of the co-operating piercers or 95 work-supporting center away from the work-piece or with the same.
64. In an apparatus or mill for rolling or forming car wheels or other circular objects, a pair of alined longitudinally movable elements, means to engage a work-piece connected to said elements and spaced apart to receive a work-piece therebetween and a stop member on one or on each of said elements having two parts and being adapted to engage a fixed part of the apparatus, one of said parts being movable with respect to the other to lengthen or shorten said stop-member and thus govern the longitudinal or axial movement of the 110 co-operating work engaging means in one direction.
65. In an apparatus or mill for rolling or forming car wheels or other circular objects, a longitudinally movable element, 115 means to engage a work-piece connected to said element and adapted to engage, pierce, penetrate, enter, center or support a work-piece, and a stop-member on said element having two parts and being adapted to engage a fixed part of the apparatus, one of said parts being movable with respect to the other to lengthen or shorten said stop-member.

ber and thus govern the longitudinal or axial movement of said work-engaging means in one direction.

61. In rolling mechanism of the kind described, three coöperating members, one a forming-die having the outer diameter of its forming portion the same or less than the diameter of the car-wheel or other article is to be when finished, the second a roll opposed to said forming-die and between which and said die a work-piece is to be rolled or formed, said roll rolling against one side of the work-piece including the side of the rim at said one side of the work-piece, and the third a peripheral face roll for rolling or forming the peripheral face of the work-piece.

62. In an apparatus or mill of the kind described, a pair of alined longitudinally movable work-supporting axles having means or being formed at adjacent ends thereof to engage a work-piece and between which means or ends a work-piece is to be positioned, a forming-die supported by one of said axles, a roll or rolls at the side of the work-piece not engaged by said forming-die adapted to cause the work-piece at the other side thereof to be formed to the shape of said die and to cause the work-piece at the side thereof not engaged by said die to be rolled to desired form or shape and means for moving said axles together longitudinally in the same direction while retaining said forming-die and said roll or rolls in fixed rotatable positions.

63. In an apparatus or mill of the kind described, a pair of alined rotatable work-supporting axles having means or being formed at adjacent ends thereof to engage a work-piece and between which means or ends a work-piece is adapted to be positioned, a forming-die at one side of said work-piece, a pair of rolls adapted to support said forming-die, at least one of said pair of rolls being adapted to act with said die to form one side of the workpiece, a side roll at the other side of the work-piece coacting with said forming-die and said one roll of said pair of rolls to roll said other side of the work-piece to desired shape including the rolling of the side of the rim or marginal portion of the work-piece at said other side, and a peripheral face roll coacting with said side roll and said one of said pair of rolls to roll or form the peripheral face of the work-piece or car-wheel or other article to desired shape.

64. Rolling mechanism comprising a forming-die, a roll or rolls in opposition to said die and between which and said die a work-piece is adapted to be positioned, means for causing relative movement of said die and said roll or rolls so as to engage opposite sides of the work-piece, means to op-

erate said roll or rolls to cause the work-piece to be shaped at opposite sides and to cause metal of the work-piece to extend beyond the periphery of said die, and rolls co-acting with said roll or rolls and together with said roll or rolls being adapted to roll the extended portion of the work-piece to desired lateral thickness and the outer peripheral face thereof to desired shape.

65. In rolling mechanism for rolling car-wheels or similar circular objects, the combination of a rotatably supported forming-die adapted to engage one side of a work-piece and having its outer peripheral forming face w^3 formed sufficiently conical substantially as and for the purpose described with Figs. 113, 116 or 117, a peripheral face roll adapted to act against the peripheral face of the work-piece, and a side roll adapted to act against the work-piece at the side thereof not engaged by said forming-die to force the work-piece against said forming-die and over the conical peripheral forming face thereof to form the side of said web engaged by said die to desired shape and to form the inner peripheral face of said rim at the side of the work-piece engaged by said die sufficiently inclined outwardly toward the peripheral face of the work-piece so as to cause metal thereof to be worked in the proper direction by the combined action of said side roll, said peripheral face roll and said conical peripheral forming-face, thereby assure compression of the metal in said rim to uniform or to practically uniform density, substantially as described.

66. In rolling mechanism of the kind described, the combination of a rotatably supported forming-die having a peripheral forming portion of suitable form to form the inner peripheral face of the marginal or rim portion at one side of the work-piece to desired form, and a roll adapted to roll against the other side of the work-piece and having a portion adapted to roll or form the inner peripheral face f^{18} of the marginal or rim portion of the work-piece at said other side thereof, said roll portion being formed sufficiently conical to roll or form said inner peripheral face f^{18} sufficiently inclined outwardly toward the outer peripheral face of the work-piece so as to cause metal for said marginal or rim portion to flow in the proper direction during the operating process of rolling or forming the work-piece or car-wheel or other similar article and to assure compression of the metal in said marginal or rim portion to uniform or practically uniform density, substantially as described with Figs. 113, 116 or 117.

67. In rolling mechanism, two coöperating parts, one a forming-die having a conically formed peripheral forming-edge surrounded

by a straight faced annular forming portion in a plane at right angles to the axis of said forming-die and whose outer diameter is the same or greater or less than the 5 diameter which the article to be rolled or formed is to be when finished, and the other a roll in opposition to said forming-die and between which and said die a work-piece is to be positioned, said roll being adapted 10 to force the work-piece against said forming-die to cause the side of the work-piece engaged by said die to be formed to desired shape by said die including the forming by said die of the side of a laterally extended 15 marginal or rim portion and to roll the other side of said work-piece to desired shape including the rolling of the other side of said laterally extended marginal or rim portion, said roll having an enlarged portion formed 20 sufficiently conical so as to roll or form the inner peripheral face of said marginal or rim portion sufficiently inclined outwardly toward the peripheral face of the work-piece to cause the metal for said marginal or 25 rim portion to flow in the proper direction during the operating process of rolling or forming the work-piece to desired form or shape and to assure compression of the metal in said marginal or rim portion to uniform 30 or practically uniform density, substantially as described.

68. Rolling mechanism comprising a forming-die having its peripheral edge formed conical, a die-supporting and edge- 35 rolling roll, and an edging and web rolling roll opposed to said forming-die and said die-supporting and edge-rolling roll, said edging and web rolling roll having a web rolling part whose inner rolling or operating 40 portion is formed sufficiently conical to roll the inner circumferential face of the rim of the work-piece with the aid of said forming-die and said die-supporting and edge-rolling roll sufficiently inclined outwardly toward 45 the peripheral face of the work-piece to cause the metal for the rim to flow in the proper direction during the operating process of rolling or forming the work-piece to desired form or shape and to assure com- 50 pression of the metal in said rim to uniform or practically uniform density substantially as described with Figs. 113, 116 or 117.

69. In an apparatus or mill for rolling or forming car wheels or other circular objects, the combination of a forming-die and 55 a pair of rolls rolling in contact with said forming-die, at least one of said rolls being positively driven and adapted to roll against the side of the rim portion of a work-piece 60 at the side thereof engaged by said die, a pair of rolls at the other side of the work-piece, at least one of said rolls being positively driven and adapted to roll said work-piece in contact with said forming-die and

to act against the other side of said rim portion, and a pair of face rolls acting against the peripheral face of the work-piece at different points thereof and adapted to coact with said two pairs of rolls to roll the rim portion of the work-piece to desired form. 65 70

70. In rolling mechanism of the kind described, the combination of a forming-die against which a work-piece is adapted to be rolled to cause said work-piece at one side thereof to be given the shape of said die, a 75 pair of rolls rolling in contact with said forming-die and at least one of said rolls being positively driven and adapted to roll against the side of the rim of said work-piece at the side thereof engaged by said die, 80 a pair of rolls rolling against the work-piece in opposition to said first-mentioned pair of rolls, at least one of said last-mentioned rolls being positively driven and a pair of peripheral face rolls between op- 85 posed rolls of said two pairs of rolls.

71. In rolling mechanism of the kind described, the combination of a forming-die against which a work-piece is adapted to be rolled, a pair of die-supporting rolls in 90 rolling contact with said die, said die and rolls being arranged at one side of the work-piece and at least one of said rolls being positively driven and having an edge rolling part, said rolls being positioned at opposite 95 sides of the axis of said die, a positively driven edging and web rolling roll opposite the die-supporting roll having the edge-rolling part and being adapted to roll the work-piece onto said forming-die to cause one side 100 thereof to be formed to the shape of said die and to roll the other side thereof to desired shape, a positively driven web finishing roll opposite the other die-supporting roll, a peripheral face rolling roll between said 105 edging and web rolling roll and said die-supporting roll having said edging roll part, and a peripheral face finishing roll between said web finishing roll and said other die-supporting roll. 11

72. In rolling mechanism, the combination of a forming-die and a pair of loosely mounted die-supporting rolls rolling in contact with the outer face of said die and being arranged at opposite sides of the axis 11 of said die, a side roll between which and said die, a work-piece is adapted to be positioned, said side roll being adapted to roll said work-piece against said die to cause one side of the work-piece to be formed to 12 the shape of the die, to cause the work-piece to be extended outwardly beyond and over the edge of said die and to roll the other side of the work-piece to desired shape and a peripheral face roll coacting with said side 1 roll and said die to roll the extended portion of the work-piece to desired form. 13

73. In an apparatus or mill for rolling or

- forming car wheels or other circular objects, the combination of a pair of alined work-supporting heads, alined axles rotatably supported in said heads and having means or being formed at adjacent ends thereof to engage a work-piece and between which means or ends a work-piece is to be supported, a forming-die supported by one of said axles, a pair of loosely mounted die-supporting rolls receiving support from the supporting head supporting said last-mentioned axle, a side roll or rolls spaced from said forming-die and adapted to roll said work-piece against said die to cause one side of the work-piece to be formed to the shape of said die and to roll the other side to desired shape.
74. In an apparatus or mill for rolling or forming car wheels or other circular objects, the combination of a pair of alined work-supporting heads, alined axles rotatably supported in said heads and having means or being formed at adjacent ends thereof to engage a work-piece and between which means or ends a work-piece is to be positioned, a forming-die supported by one of said axles, a pair of brackets extending from the supporting head supporting said last-mentioned axle, a roll loosely mounted in each of said brackets said rolls being adapted to roll in contact with said forming-die at opposite sides of its axis, a side roll or rolls spaced from said forming-die and being adapted to roll said work-piece against said die to cause one side of the work-piece to be formed to the shape of said die and to roll the other side thereof to desired shape.
75. In an apparatus or mill for rolling or forming car wheels or other circular objects, the combination of a pair of alined work-supporting heads, one of which at least is longitudinally movable, alined axles rotatably supported in said heads and having means or being formed at adjacent ends thereof to engage a work-piece and between which means or ends a work-piece is to be positioned, a forming-die supported by the axle supported in said longitudinally movable head, a pair of loosely mounted die-supporting rolls receiving support from said longitudinally movable head and adapted to roll in contact with said forming-die, said rolls being movable with said head, a side roll or rolls spaced from said forming-die and being adapted to roll said work-piece against said die to cause one side of the work-piece to be formed to the shape of said die and to roll the other side thereof to desired shape.
76. In an apparatus or mill for rolling or forming car wheels or other circular objects, the combination of a pair of alined longitudinally movable work-supporting heads, alined axles rotatably supported in
- said heads and having means or being formed at adjacent ends thereof to engage a work-piece and between which means or ends a work-piece is to be supported, said axles being longitudinally movable with said heads, a forming-die supported by one of said axles and rotatable therewith, a pair of loosely mounted die-supporting rolls receiving support from one of said supporting heads, one or both of said die supporting rolls being adapted to roll in contact with the side of the rim portion of the work-piece at the side thereof engaged by said die, a side roll spaced from said forming-die and being adapted to roll said work-piece against said die to cause one side of the work-piece to be formed to the shape of said die and to roll the other side of the work-piece to desired shape, said side roll being opposed to one of said loosely mounted supporting rolls, and a second side roll opposed to the other of said loosely mounted supporting rolls and adapted to roll said other side to finish.
77. In an apparatus or mill for rolling or forming car-wheels or other circular objects, a pair of alined longitudinally movable work-supporting heads, alined axles rotatably supported in said heads and having means or being formed at adjacent ends thereof to engage a work-piece and between which means or ends a work-piece is to be positioned, at least one of said axles being movable longitudinally independently of its supporting head, a forming-die supported by the axle which is movable independently of its said head, brackets extending from opposite sides of said supporting head, a pair of loosely mounted die-supporting rolls located between said brackets and rolling in contact with said die, one of said loosely mounted rolls being also adapted to roll the side of the rim portion of the work-piece at the side thereof engaged by said die, a side roll spaced from said forming-die at one side of the axis of said die and being adapted to roll said work-piece against said die to cause one side thereof to be formed to the shape of said die and to cause the work-piece to be extended outwardly beyond and over the peripheral edge of said die and to roll the other side of the work-piece to desired shape, said side roll being opposed to one of said loosely mounted rolls, a second side roll opposed to the other of said loosely mounted rolls and adapted to roll said other side or a part of said other side of the work-piece to finish, a peripheral face rolling roll adapted to roll the peripheral face of the extended or rim portion of the work-piece to desired form and coacting with said first-mentioned side roll and one of said loosely mounted rolls to roll the metal in the extended or rim portion of the work-piece to

uniform or practically uniform density, and a second peripheral face roll coacting with said second side roll and with the other of said loosely mounted rolls to roll said extended or rim portion to finish.

78. In an apparatus or mill for rolling or forming car wheels or other circular objects, the combination of a pair of aligned longitudinally movable work-supporting heads, aligned work-supporting axles rotatably supported in said heads and having means or being formed at adjacent ends thereof to engage a work-piece and between which means or ends a work-piece is to be positioned, at least one of said axles being longitudinally movable with or independent of its supporting head, a forming-die rotatably supported by said last-mentioned axle, a pair of loosely mounted die-supporting rolls receiving support from the supporting head supporting said last-mentioned axle and rolling in contact with said die, and a roll opposed to said die and adapted to roll said work-piece thereagainst.
79. In an apparatus or mill for rolling or forming car wheels or other circular objects, the combination of a pair of aligned longitudinally movable work-supporting heads, aligned work-supporting axles rotatably supported in said heads and having means or being formed at adjacent ends thereof to engage a work-piece and between which means or ends a work-piece is to be positioned, at least one of said axles being longitudinally movable independent of its supporting head, a forming die supported by one of said axles, means for rotatably supporting said forming die at opposite sides of said axles, and a roll or rolls opposed to said die and adapted to roll said work-piece against said die.
80. In an apparatus or mill for rolling or forming car-wheels or other circular objects, the combination of a pair of aligned longitudinally movable work-supporting heads, aligned work-supporting axles rotatably supported in said heads, a pair of rolls receiving support from one of said heads and being arranged at opposite sides of the axle supported by said head, a forming-die supported by said axle, said rolls rolling in contact with said forming-die, a pair of side rolls opposed to said forming-die and between which side rolls and said forming-die the work-piece is located, said side rolls being at opposite sides of the axis of the work-piece, and a pair of peripheral face rolls at opposite sides of said axis adapted to act against the peripheral face of the work piece either together or independent of each other.
81. In an apparatus or mill for rolling or forming car wheels or other circular objects, the combination of a forming-die

against which a work-piece is to be rolled, a support having a portion on which said die is mounted, a pair of loosely mounted rolls carried by said support and acting against the outer side of said die at opposite sides of its axis, a pair of side rolls arranged at the side of the work-piece not engaged by said forming-die and being positioned at opposite sides of the axis of the work-piece, said side rolls being movable toward and from said forming-die and one of said side rolls being adapted to extend metal of the work-piece outwardly beyond the peripheral edge of said forming-die and over the same, and a pair of peripheral face rolls acting together or independently of each other to roll the peripheral face of the extended or marginal portion of the work-piece, said loosely mounted rolls being movable with said forming-die and said support in the direction of the axis of the work-piece.

82. In an apparatus or mill for rolling or forming car wheels or other circular objects, a longitudinally movable element, means connected to said element and adapted to engage a work-piece, and a stop member on said element having movable parts adapted to lengthen or shorten said stop member whereby said element may be stopped at a plurality of different points, said stop-member being adapted to engage a fixed part of the apparatus.

83. In an apparatus or mill for rolling or forming car wheels or other circular objects, longitudinally movable means to engage a work-piece, and a stop-member operatively connected to said means and having movable parts adapted to lengthen or shorten said stop-member whereby said means may be stopped in its longitudinal movement at any one of a plurality of predetermined points.

84. In an apparatus or mill for rolling or forming car wheels or other circular objects, a longitudinally movable element, means connected to said element and adapted to engage a work-piece, and a stopping device on said element comprising a sleeve and a plurality of movable parts adapted to be swung into or out of line with said sleeve and engage a fixed part of the apparatus to govern the length of movement of said element.

85. In an apparatus or mill for rolling or forming car wheels or other circular objects, a longitudinally movable element, means connected to said element and adapted to engage a work-piece, a stopping device on said element comprising a fixed member and a plurality of movable members to be moved into or out of line with said fixed member to determine any one of a plurality of stopping points and thereby govern the length of movement of said element, said fixed

member or any of said movable members being adapted to engage a fixed part of the apparatus.

86. In an apparatus or mill for rolling or forming car wheels or other circular objects, alined means to engage a work-piece positioned therebetween, a pair of longitudinally movable rods to each of which one of said engaging means is attached, a stopping-device 10 vice detachably secured to each of said rods and comprising a sleeve and a plurality of pivoted parts adapted to be swung into line with said sleeve to lengthen the same, said sleeve or any of said pivoted parts when 15 swung into line with said sleeve being adapted to engage a fixed part of the apparatus to govern the extent of longitudinal or axial movement of said engaging means.

87. In an apparatus or mill for rolling or forming car wheels or other circular objects, the combination of a pair of alined longitudinally movable work-supporting axles having means or being formed at adjacent ends thereof to engage a work-piece and between which means or ends a work-piece to be rolled is adapted to be positioned, means for moving said axles toward each other to axially clamp the work-piece, a forming-die at one side of the work-piece supported by 25 one of said axles, a pair of die-supporting rolls supporting said die at opposite sides of its axis, one of said die-supporting rolls being provided with an edging roll part, said forming-die and said pair of die supporting rolls being removable, an edging and web rolling roll at the other side of the work-piece adapted to roll said work-piece against said forming-die and to extend the metal of the work-piece outwardly beyond 30 and over the peripheral edge of said die and into engagement with the edge-rolling part of said die-supporting roll, a web finishing roll adapted to act against said other side of the work-piece, a peripheral face rolling 35 roll adapted to act against the peripheral face of the work-piece between the edging roll part of said die-supporting roll and said edging and web rolling roll and serving with said two last-mentioned rolls to 40 roll the rim portion of the work-piece to desired form, a peripheral face finishing roll between the other die-supporting roll and said web finishing roll and adapted to roll said rim portion to finish, 45 an edging and web rolling roll and a web finishing roll adapted to be substituted for said forming-die and said die-supporting rolls and together with said first-mentioned edging and web rolling roll and said first-mentioned web finishing roll acting to retain 50 the marginal or rim portion of the work-piece in rotatable position while moving said work-supporting axles together longitudinally in one direction for dishing the car 55 wheel.

88. An apparatus or mill for rolling or forming car wheels or other circular objects, comprising a pair of axially alined work-supporting axles having means or being formed at adjacent ends thereof to engage 70 a work-piece and between which means or ends a work-piece is adapted to be positioned, a forming-die supported by one of said axles, a die-supporting roll in contact with the outer side of said die at one side of 75 its axis, said die-supporting roll having an edging roll part in contact with the peripheral edge of said forming-die, a side roll spaced from said forming-die and adapted to roll the work-piece against said die and to force metal thereof outwardly over and beyond the peripheral edge of said die and into contact with the edging roll part of said die-supporting roll, a peripheral face rolling roll between said edging roll part and said side roll and adapted to act against the outer peripheral face of the extended or rim portion of the work-piece and against the opposite sides of which face roll said edging roll part and said side roll rotate, 80 and a peripheral face finishing roll engaging the outer peripheral face of said extended or rim portion at another point thereof to roll the outer peripheral face of said extended or rim portion to finish. 85

89. An apparatus or mill for rolling or forming car wheels or other circular objects, comprising a pair of alined work-supporting axles having means or being formed at adjacent ends thereof to engage a work-piece and between which means or ends a work-piece is adapted to be positioned, a forming-die carried by one of said axles and having a central hub forming cavity, a die-supporting roll engaging the outer side 90 of said die at one side of its axis and having an edging roll part extending outwardly from the peripheral edge of said die, a side roll opposite said die-supporting roll and adapted to work metal of the work-piece 95 into said hub forming cavity and to roll the work-piece against the remaining portion of said die and force metal thereof outwardly over and beyond the peripheral edge of said die and into contact with the edging roll part of said die-supporting roll, a peripheral face rolling roll between said edging roll part and said side roll adapted to act against the peripheral face of the extended or rim portion of the work-piece and against the opposite sides of which face roll said edging roll part and said side roll rotate, and a peripheral face finishing roll engaging the outer peripheral face of said rim portion during or after the forming thereof by said side roll, said peripheral face rolling roll and said edging roll part, said peripheral face finishing roll being adapted to roll the outer peripheral face of said rim portion to finish. 100

90. An apparatus or mill for rolling or forming car wheels or other circular objects, comprising a pair of aligned work-supporting axles having means or being formed at adjacent ends thereof to engage a work-piece and between which means or ends a work-piece is adapted to be positioned, a forming-die supported by one of said axles and having a central hub-forming cavity and a conical portion at its peripheral edge, a die-supporting roll engaging the outer side of said die at one side of its axis and having an edging roll part extending outwardly from the peripheral edge of said die, a side roll opposite said die-supporting roll having a web rolling part provided with an inclined rolling face adapted to roll the inner peripheral face of the rim portion of the work-piece and having an edging roll part in opposition to the edging roll part of said die-supporting roll, the web rolling part of said side roll being adapted to force metal of the work-piece into said hub-forming cavity and to roll the work-piece against the remainder of the forming face of said die while reducing the thickness of the work-piece where desired to form the web and to extend metal of the work-piece outwardly to form the rim, a peripheral face rolling roll in contact with the outer peripheral face of the extended portion of the work-piece, said peripheral face rolling roll being reduced in diameter at one side and having the edging roll parts of said die-supporting roll and of said side roll in rolling contact with part of its opposite sides, the edging roll part of said side roll with the reduced portion of said peripheral face rolling roll forming a flange on said rim portion, and a peripheral face rolling roll at another point of the rim portion adapted to roll against the peripheral face and portions of the opposite edges of the rim portion to roll the same to finish.

91. An apparatus or mill for rolling or forming car wheels or other circular bodies, comprising a pair of aligned work-supporting axles having means or being formed at adjacent ends thereof to engage a work-piece and between which means or ends a work-piece is adapted to be supported, a forming-die supported by one of said axles and having a conical portion at its peripheral edge, a die-supporting roll rolling in contact with the outer side of said die at one side of its axis and extending beyond the peripheral edge of said die, a rolling roll opposite said die-supporting roll adapted to roll the work-piece against said die to cause one side of the work-piece to be formed to desired shape by said die and to cause metal of the work-piece to be rolled outwardly beyond and over the peripheral edge of said die, and a peripheral face rolling roll adapted to act against the outer

peripheral edge face of the work-piece, said rolls being adapted to act to force the metal in the rim toward each other and toward the conical portion of said die, thus compressing the metal in said rim portion to uniform or practically uniform density.

92. An apparatus or mill for rolling or forming car-wheels or other circular objects, having a pair of aligned rotatable axles provided with piercers or centers at adjacent ends, at least one of said piercers or centers having an outwardly facing shoulder, a forming-die on said last mentioned piercer or center having a hub-forming cavity into which said piercer or center extends and against the inner end wall of which the shoulder of said piercer or center bears, means in contact with the outer side of said forming-die to rotatably support said die, means for exerting pressure against said axles to cause said piercers or centers to axially penetrate or pierce the work-piece, a side roll or rolls spaced from said forming-die and adapted to roll or force metal of the work-piece into said hub-forming cavity and around said piercers or centers to form the hub of the work-piece and to roll the work-piece against said die so as to form the side of the work-piece engaged by said die to desired shape by said die while reducing the thickness of the work-piece where desired to form the web portion thereof, and a peripheral face rolling roll or rolls co-acting with said die and said side roll or rolls to form the rim portion of the work-piece.

93. An apparatus or mill for rolling or forming car wheels or other circular objects, comprising a rotatably supported die and a longitudinally movable side roll spaced from said die, said die and roll being relatively movable to approach one another and being adapted to have a work-piece positioned there-between, said side roll being adapted to act to roll the work-piece against said die and cause the work-piece to be formed at one side to the shape of said die and to roll the other side of the work-piece to desired shape including the rolling of the side of the marginal or rim portion of the work-piece at said other side, means for moving said side roll radially with respect to the work-piece, and means for positively rotating said side roll or a part or parts thereof.

94. An apparatus or mill for rolling or forming car wheels or other circular objects, comprising a rotatably supported forming-die against which a work-piece having an extended rim is adapted to be positioned, said die engaging the inner peripheral face of said rim at one side of the work-piece, a side roll spaced from said die and adapted for movement toward and from the same, said side roll having a web rolling part

adapted to roll against the inner peripheral face of said rim at the other side of the work-piece, and a peripheral face roll having an inclined or conical rolling portion 5 adapted to roll the tread of the work-piece, an annular groove adjacent said inclined or conical rolling portion adapted to roll a flange on the peripheral face of the work-piece and two flanges between which said 10 inclined or conical rolling portion and said annular groove are located, said flanges acting against portions of opposite edges of the rim of the work-piece.

95. An apparatus or mill for rolling or forming car wheels or other circular objects, comprising a pair of alined rotatable axles between which a work-piece is adapted to be supported, a forming-die rotatably mounted on one of said axles, a pair of die-supporting rolls rolling in contact with said forming-die at opposite sides of its axis and one of said rolls having an edging roll part 20 in contact with a portion of the peripheral edge of said forming-die, a side roll opposite the other die-supporting roll adapted to roll in contact with the work-piece to force the same into and against said forming-die and over the peripheral edge thereof, said side roll being also adapted to act to reduce 25 the thickness of the work-piece where desired to force metal thereof toward the axis of the work-piece to form the hub and to force metal outwardly to form the rim of the work-piece, a side roll opposite the die-supporting roll having said edging roll part and adapted to act with said edging roll part to roll the opposite sides of said rim, and a peripheral face rolling roll between 30 said first-mentioned side roll and said second-mentioned die-supporting roll for rolling the rim portion with a finished tread and flange.

96. An apparatus or mill for rolling or forming car wheels or other circular objects, comprising a pair of alined rotatable axles having centers or piercers at adjacent ends between which a work-piece is adapted to be supported, a forming-die mounted on one of said axles, a die-supporting roll engaging the outer side of said forming-die at one side of its axis, a side roll opposite said die-supporting roll adapted to force the work-piece against said die to cause one side of said work-piece to be formed to the shape 55 of said die and to roll said work-piece to reduce the thickness thereof where desired and form a web portion, to force metal toward the axis of the work-piece to form a hub portion and to force metal outwardly 60 to form a rim portion, a peripheral face rolling roll in contact with the rim portion of the work-piece, and means for moving said axles longitudinally together independently of said forming-die, its supporting roll and 65 said side and face rolls.

97. An apparatus or mill for rolling or forming car wheels or other circular objects, comprising a pair of alined rotatable axles having centers or piercers at adjacent ends between which a work-piece is adapted to be supported, a forming-die mounted on one of said axles, a die-supporting roll engaging the outer side of said forming-die at one side of its axis, a side roll spaced from said forming-die and adapted to be moved toward said die to force the work-piece thereagainst and cause one side of the work-piece to be formed to the shape of said die and to roll said work-piece to reduce the thickness thereof where desired to form a web portion 80 and to force metal of the work-piece outwardly to form a rim portion, a peripheral face rolling roll in contact with the rim portion of the work-piece, and means for moving said axles longitudinally together independently of said forming-die, its supporting roll and said side and face rolls.

98. An apparatus or mill for rolling or forming car wheels or other circular objects, comprising a pair of alined rotatable axles 90 having centers or piercers at adjacent ends between which a work-piece is adapted to be supported, said centers having flanges and being adapted to pierce or penetrate or enter the work-piece to cause said flanges to 95 engage opposite sides of the work-piece at its central portion, a forming-die mounted on one of said axles and having a hub-forming cavity against the inner end wall of which the flange of the center or piercer of 100 said axle bears, a die-supporting roll engaging the outer side of said forming-die at one side of its axis and having an edging roll part engaging the peripheral edge of said forming-die with its inner end, a side roll 105 spaced from said forming-die and adapted to be moved toward said die to force the work-piece thereagainst and cause one side of the work-piece to be formed to the shape of said die and also to roll said work-piece 110 to reduce the thickness thereof where desired to form a web portion and to force metal of the work-piece outwardly beyond and over the peripheral edge of said forming-die and against the edging roll part of said die-supporting roll, said side roll being also adapted to act to force metal of the work-piece into said hub-forming cavity, a peripheral face rolling roll between the edging roll part of said die-supporting roll and said side 115 roll, said face rolling roll being adapted to act against the peripheral face of the metal extended outwardly by said side roll and having said side roll and the edging roll part of said die-supporting roll in rolling contact therewith, and means for moving said work-supporting axles longitudinally together independently of said forming-die, its supporting roll and said side and face rolls.

99. An apparatus or mill for rolling or forming car wheels or other circular objects, comprising a pair of aligned rotatable axles having piercers or centers at adjacent ends between which a work-piece is adapted to be supported, a forming-die mounted on one of said axles or on one of said piercers or centers, a die-supporting roll engaging the outer side of said forming-die at one side of its axis and having an edging roll part engaging the peripheral edge of said forming-die with its inner end, a side roll spaced from said forming-die and arranged for longitudinal movement and for movement toward and from said forming-die, said side roll being adapted to act to force the work-piece against said die to form the work-piece at one side thereof to the shape of said die and also to roll said work-piece at the other side thereof to reduce the thickness of the work-piece where desired to form a hub portion and to extend metal of the work-piece outwardly beyond and over the peripheral edge of said forming-die and against the edging roll part of said die-supporting roll, a peripheral face roll between the edging roll part of said die-supporting roll and said side roll, said face roll acting against the peripheral face of the metal extended outwardly by said side roll and having said side roll and the edging roll part of said die-supporting roll in rolling contact therewith, said face roll coacting with the edging roll part of said die-supporting roll, with the peripheral edge of said forming-die and with said side roll to roll the extended or marginal portion of the work-piece into the form of a flanged rim, a second peripheral face roll acting against the peripheral face of said flanged rim to roll the same to finish, and means for moving said axles longitudinally together independently of said die, its supporting roll and said face rolls and side roll.
- 45 100. An apparatus or mill for rolling or forming car wheels or other circular objects, comprising a pair of aligned rotatable axles for supporting a work-piece there-between, a forming die mounted on one of said axles and rotatable therewith, a pair of die-supporting rolls rolling in contact with said forming-die at opposite sides of its axis, one of said die-supporting rolls having an edging roll part in contact with a portion of the peripheral edge of said forming-die, a side roll opposite the other die-supporting roll adapted to roll in contact with the work-piece to force the same against said forming-die and over the peripheral edge thereof, said side roll being also adapted to reduce the thickness of the work-piece where desired to force metal toward the axis of the work-piece to form the hub and to force metal outwardly to form the rim of the work-piece, a side roll opposite the die-sup-
- porting roll having said edging roll part and adapted to act with said edging roll part to roll opposite sides of said rim, a peripheral face rolling roll between said first-mentioned side roll and said second-mentioned die-supporting roll for rolling the rim portion with a finished tread and flange, and means for moving said axles longitudinally together independently of said forming-die and said rolls.
- 105 101. An apparatus or mill for rolling or forming car wheels or other circular objects, comprising a pair of aligned axles having means or being formed at adjacent ends thereof to engage a work-piece and between which means or ends a work-piece is adapted to be supported, a forming-die supported by one of said axles at one side of the work-piece, die-supporting rolls engaging said forming-die at diametrically opposite points, rolls at opposite sides of the work-piece adapted to coat with said forming-die to form opposite sides of the work-piece, a peripheral face roll adapted to act against the peripheral face of the work-piece, and means for moving said work-supporting axles longitudinally together while retaining said forming die and said rolls in rotatable positions.
- 110 102. In rolling mechanism, the combination of a forming-die, a pair of die-supporting rolls adapted to support said forming-die, one of which is provided with an edging roll part adapted to roll in contact with one side of the rim of the work-piece, a side roll spaced from the forming face of said die and between which and said die the work-piece is adapted to be positioned, and a peripheral face roll positioned between said side roll and the edging roll part of said separately-mentioned die-supporting roll and having a width equaling that which the width of the rim of the work-piece is to be when finished.
- 115 103. In an apparatus or mill for rolling or forming car wheels or other circular objects, a pair of aligned rotatable work-supporting axles between which a work-piece is adapted to be positioned, a forming-die supported by one of said axles, a die-supporting roll rolling in contact with the outer side of said die and having an edging roll part extending outwardly from the peripheral edge of said die, a side roll adapted to roll the work-piece against said die to cause one side of the work-piece to be formed to the shape of said forming-die and to force metal of the work-piece outwardly over the peripheral edge of said die and against the edging roll part of said die-supporting roll, and a face roll adapted to operate against the peripheral face of the outwardly forced metal of said work-piece and being positioned between said die-supporting roll and said side roll, said die-supporting roll and

said side roll rolling in contact with said face roll and said face roll having a width equaling that which the rim of the article will have when completed.

5 104. In an apparatus or mill for rolling or forming car wheels or other circular objects, a pair of aligned rotatable work-supporting axles between which a work-piece is to be positioned, a forming-die supported by one 10 of said axles, a die-supporting roll rolling in contact with the outer side of said die at one side of its axis and having an edging roll part extending outwardly from the peripheral edge of said die, a side roll adapted to roll the work-piece against said die and to force metal over the edge of said die and against the edging roll part of said die-supporting roll, said side roll being also adapted to roll the side of said work-piece 15 engaged thereby to form a web and a rim portion and to roll in contact with said rim portion, a peripheral face roll having a reduced portion at one side thereof and rolling in contact with the peripheral face of the work-piece, said side roll and the edging roll part of said die-supporting roll rolling in contact with parts of the opposite sides of said face roll and the reduced portion of said face roll serving to form a flange 20 on the tread of the work-piece.

105. In an apparatus or mill for rolling or forming car-wheels or other circular objects, a pair of aligned rotatable and longitudinally movable work-supporting axles, a forming-die coaxial with said axles and supported by one of said axles, rolls co-operating with said forming-die to roll the work-piece into the form of a car-wheel or other circular object having a hub, a web and a rim, and means for moving said work-supporting axles longitudinally together in one direction while the work-piece is rotated by at least one of said rolls and the marginal or rim portion of the work-piece is supported and retained by means of said die and said rolls or by means of said die and at least one of said rolls.

106. In an apparatus or mill for rolling or forming car wheels or other circular objects 50 a forming-die having a forming-face against which a work-piece is to be rolled and having also an annular groove on the face opposite said forming-face, a die-supporting roll having a flange or die-supporting portion rolling in said groove, a side roll acting against the work-piece to cause the same to be given the shape of said forming-face and to roll metal of the work-piece outwardly beyond the peripheral edge of said die, a face roll adapted to act against the peripheral face of the outwardly forced metal to roll said face to the form of a flanged tread, and a second face roll acting against said flanged tread to roll the same to finish.

65 107. In rolling mechanism, the combina-

tion of a forming-die having an annular groove in its outer face, a die-supporting roll having a peripheral flange or die-supporting portion fitting said groove, and a side roll spaced from said die and adapted 70 to roll the work-piece thereagainst so as to form the same at one side to the shape of said die and to roll the same at the other side to desired shape.

108. In rolling mechanism, the combination of a forming-die having an annular groove in its outer face adjacent its peripheral edge, a die-supporting portion having a peripheral groove adapted to receive the portion of the die between its annular 80 groove and the peripheral edge thereof, and a side roll spaced from said die and adapted to roll the work-piece thereagainst so as to form the same at one side to the shape of said die and to roll the same at the other 85 side to desired shape.

109. In an apparatus or mill for rolling or forming car wheels or other circular objects, the combination of a pair of work-supporting axles between which a work-piece is to be positioned, a forming-die coaxial with said work-supporting axles and against which the work-piece is to be rolled, a die-supporting roll rolling in contact with the outer side of said die and having an edging 90 roll part extending outwardly from the peripheral edge of said die, a side roll adapted to act against the side of the work-piece not engaged by said die to force the work-piece against said die and to 100 roll and reduce the thickness of the work-piece where desired to form a web and force metal of the work-piece outwardly beyond the peripheral edge of said die to form a rim, a peripheral face roll positioned 105 between said side roll and the edging roll part of said die-supporting roll and having a width determining that of said rim, said face roll having a reduced portion at one side for rolling a partly formed flange upon 110 said rim, and a second peripheral face roll spaced from said first-mentioned peripheral face roll for rolling the peripheral face of said rim including said flange to finished form.

110. In rolling mechanism, three co-operating rolls, one a peripheral face roll having a reduced portion at one side and being adapted to roll against the peripheral face of a work-piece, the remaining rolls acting 120 against opposite sides of the rim of the work-piece and against opposite sides of said face roll, said reduced portion of said face roll coacting with one of said side rolls to form a groove or pass for rolling a flange or 125 a rudimentary flange on said rim.

111. In rolling mechanism, three co-operating rolls, one a peripheral face roll having a reduced portion at one side thereof and being adapted to roll against the pe- 130

5 peripheral face of a work-piece, the others being side rolls acting against opposite sides of the rim of the work-piece and against opposite sides of said face roll, one of said 10 side rolls meeting the adjacent side of the reduced portion of said peripheral face roll to form a sharp angle and with the reduced portion of said face roll forming a rolling groove or pass into which metal of the work-piece is rolled to form a flange on the peripheral face of the work-piece, said flange having a sharp angle formed by the peripheral edge thereof and the side of the work-piece, and a second peripheral face roll having 15 a rounded annular groove and being adapted to roll in contact with the peripheral face of the work-piece as formed by said first-mentioned peripheral face roll and to roll the angular portion of said flange to 20 rounded form and the remaining portion of the tread of the work-piece to finished form.

112. In rolling mechanism, the combination of a pair of aligned longitudinally movable work-supporting axles having means or being formed at adjacent ends thereof to engage a work-piece and between which means or ends a work-piece is to be positioned, a forming-die adapted to be positioned at one side of the work-piece and to be rotatably supported in coaxial relation with said work-supporting axles, a roll adapted to operate against the other side of the work-piece, and, means for moving 30 said work-supporting axles longitudinally together in one direction independently of said forming-die and said roll.

113. In an apparatus or mill for rolling or forming car-wheels or other circular objects, the combination of a pair of aligned longitudinally movable work-supporting axles having means or being formed at adjacent ends thereof to engage a work-piece and between which means or ends the work-piece 40 is to be supported, a forming-die adapted to be positioned at one side of said work-piece and being coaxial with said work-supporting axles, a shaft at one side of a plane passing circumferentially through the work-piece, a die-supporting roll on said shaft in rolling contact with the outer side of said die and having an edging roll part with a straight peripheral face extending outwardly from the peripheral edge of said die, a 45 shaft at the other side of said plane, a forming-roll on said last-mentioned shaft having a web rolling part and an edging roll part provided with a straight peripheral face, said forming-roll being adapted to act 55 against the other side of the work-piece to roll the work-piece against said forming-die and cause the side of the work-piece engaged by said die to be formed to the shape of said die and to roll metal of the work-piece outwardly beyond the peripheral edge of said 60

70 die and against the edging part of said die-supporting roll and to roll the side of the work-piece engaged by said forming-roll to form the web or a portion thereof and to roll in contact with the side of the extended or marginal portion of the work-piece, a peripheral face roll in contact with the peripheral face of the extended or marginal portion of the work-piece and having the edging roll parts of said side roll and said die-supporting roll in rolling contact with the opposite sides of the marginal portion of said face roll, said face roll having a reduced portion at one side against which metal of the work-piece is to be rolled to form a flange on the 80 outer peripheral face of the extended or marginal portion of the work-piece, a peripheral face roll spaced from said first-mentioned face roll and adapted to roll said flanged peripheral face to finished form, 85 and means for moving said work-supporting axles longitudinally together independently of said die and said rolls.

114. In an apparatus or mill for rolling or forming car wheels or other circular objects, a pair of aligned work-supporting axles, a rotatably mounted forming-die coaxial with said axles and against which a work-piece supported between said axles is to be rolled, and a side roll adapted to roll the 90 side of the work-piece opposite said die to desired shape, said axles and said die with said roll being relatively movable in the direction of the axis of the work-piece to dish the latter.

115. In an apparatus or mill for rolling or forming car wheels or other circular objects, a pair of aligned work-supporting axles having means or being formed at adjacent ends thereof to engage a work-piece and between 105 which means or ends a work-piece is to be supported, a rotatably mounted forming-die coaxial with said axles and against which the work-piece is to be rolled, a die-supporting roll in rolling contact with said die and 110 having an edging roll part extending outwardly from the peripheral edge of said die, and a side roll adapted to roll the side of the work-piece not engaged by said die to desired shape, and said side roll with said die 115 and the edging roll part of said die-supporting roll retaining the marginal or rim portion of the work-piece against lateral movement, and means for moving said work-supporting axles axially together for dishing 120 the work-piece while so retaining the marginal portion thereof.

116. In rolling mechanism, the combination of rotatably supported forming-die having a forming-face at one side thereof 125 against which a work-piece is to be rolled and having a circular supporting face at the marginal portion of its other side formed with an outwardly facing shoulder, and a die-supporting and edge rolling roll 130

formed of two straight faced portions forming an inwardly-facing shoulder in contact with the outwardly facing shoulder of said forming-die, said die-supporting and edge 5 rolling roll having its die-supporting portion arranged to roll in contact with the circular supporting face of said forming-die and having its edge rolling portion adapted to roll against or in contact with the side 10 of the marginal or peripheral portion of the work-piece extending outwardly from the peripheral edge of said forming-die.

117. In rolling mechanism, the combination of a rotatably mounted forming-die 15 adapted to engage one side of a work-piece, a supporting roll in rolling contact with said die and having an edging roll part in contact with the peripheral edge of said die and forming a sharp angle therewith, a side roll 20 spaced from said forming-die and between which and said die a work-piece is to be rolled, said side roll being adapted to roll in contact with said work-piece at the side thereof not engaged by said forming-die so 25 as to roll said work-piece against said die and to cause metal thereof to be extended outwardly over the peripheral edge of said die, into the angle formed by said peripheral edge and the edging roll part of said die- 30 supporting roll and against said edging roll part, and a peripheral face roll between said side roll and the edging roll part of said die- supporting roll and having said side roll and said edging roll part rolling in contact 35 with opposite sides thereof, said side and face rolls and said die and the edging roll part of said supporting roll being adapted to form a rim portion on the work-piece without fins or other objectionable project- 40 ing parts.

118. In rolling mechanism of the kind described, a forming-die having a definite outer diameter determining the inner diameter of the rim of the work-piece at the side 45 thereof next to said die and against which forming-die the work-piece is to be rolled so that the side of the work-piece engaged by said die from the inner peripheral face of the rim portion to and including the per- 50ipheral face of the hub portion of the same side of the work-piece is formed to desired shape by said die, and rolls for so rolling the work-piece against said die and for roll- 55 ing the remainder of the work-piece includ- ing the rolling of the opposite sides of the rim as desired and the outer peripheral face thereof to desired shape.

119. In an apparatus or mill for rolling or forming car wheels or other circular ob- 60 jects, the combination of a pair of alined work-supporting axles adapted to support a blank or other work-piece having a central hole, one of said axles having a bore and the other being adapted to be moved through 65 the hole of the work-piece and enter said

bore, and means for forming or rolling the work-piece to desired shape.

120. In an apparatus or mill for rolling or forming car wheels or other circular ob- 70 jects, the combination of a pair of alined rotatable work-supporting axles provided with centers at adjacent ends adapted to support a blank or other work-piece having a central conical hole, one of said centers having an axial bore and the other having a 75 tapered portion terminating in a cylindrical end portion adapted to enter said axial bore, said tapered portion and cylindrical end portion being entered in the central conical hole of the work-piece, and means for forming or rolling the work-piece thus supported to desired shape. 80

121. In an apparatus or mill for rolling or forming car wheels or other circular ob- 85 jects, a pair of alined work-supporting axles for supporting a work-piece, said axles being provided with coacting means whereby one of said axles is connected with the other to provide a substantial support for the work-piece, and means for rolling or forming a work-piece thus supported to desired 90 shape. 95

122. In an apparatus or mill for rolling or forming car wheels or other circular ob- 100 jects, a pair of alined work-supporting axles for supporting a work-piece, said axles having male and female connecting parts adapted to be brought into coöperation when supporting the work-piece, and means for rolling or forming the work-piece thus supported to desired shape. 100

123. In an apparatus or mill for rolling or forming car wheels or other circular ob- 105 jects, the combination of a pair of alined work-supporting axles having supporting centers at adjacent ends, one of said centers having a tapered portion and a cylindrical end portion adjacent said tapered portion and being adapted to enter or be forced into a work-piece having a central hole, the other center having a bore whose axis is coincident with the axis of said cylindrical end portion, said bore being adapted to receive said cylindrical end portion, a forming-die 110 mounted on one of said centers and adapted to have the work-piece rolled thereagainst to form one side thereof to the shape of said die, and rolls coacting with said die to roll or form the work-piece to desired shape. 115

124. An apparatus or mill of the kind de- 120 scribed, comprising a forming-die against which a portion of one side of the work- piece is adapted to be formed, and rolls ar- ranged in a plane extending laterally through the work-piece and forming-die and adapted to roll the remaining portion of the side of the work-piece at the side thereof engaged by said die, the outer peripheral face and the other side of the work-piece to 125 desired shape, at least one of said rolls be- 125

ing also adapted to roll the work-piece against said die.

125. An apparatus or mill for rolling or forming car wheels or other circular objects, comprising a forming-die having a central hub-forming cavity and into and over which a work-piece is adapted to be rolled so as to form the side of the work-piece engaged by said die with a hub portion, a web portion and to form the inner peripheral face of the rim portion at the same side thereof, and a plurality of rolls arranged in a plane passing laterally through the work-piece and die and adapted to so roll the work-piece against said die and to surround and roll the remainder of the rim portion of the work-piece, at least one of said rolls being adapted to act against the side of the work-piece not engaged by said die to roll the same from said rim portion inwardly toward the axis of the work-piece.

126. An apparatus or mill for rolling or forming car wheels or other circular objects, comprising means for centrally and rotatably supporting a work-piece from opposite sides thereof, a plurality of rolls arranged in a plane passing laterally through the work-piece and adapted to completely roll one side of the work-piece, to roll the side of the rim portion at the other side of the work-piece and to roll the outer peripheral face of the work-piece, and a forming-die co-axial with said supporting means and having its forming face adapted to form the remainder of said other side of the work-piece through the rolling action of at least one of said rolls.

127. In an apparatus or mill for rolling or forming car wheels or other circular objects, the combination of a pair of alined axles having work-supporting centers at adjacent ends, one of said centers having an axial bore adapted to receive the end of the other center, said last-mentioned center being adapted to extend through a work-piece having a central hole, a forming-die on one of said centers having a hub-forming cavity and against which the work-piece is adapted to be rolled, and a side roll adapted to engage the work-piece at the side thereof not engaged by said forming-die and having its end operating in contact with said bored center, said roll being adapted to force metal of the work-piece with its peripheral portion into said hub-forming cavity and to roll the work-piece over said forming-die to desired shape.

128. In an apparatus or mill for rolling or forming car wheels or other circular objects, the combination of a pair of alined axially movable axles having work-supporting centers by means of which a work-piece having a central hole is adapted to be supported, one of said centers having an en-

larged cylindrical portion, a reduced tapered portion adjoining said cylindrical portion and providing an inwardly facing shoulder at the inner end of said cylindrical portion and a reduced cylindrical end portion, the other center having an axial bore into which said reduced cylindrical end portion is entered, said first-mentioned center being adapted to be entered or forced into and extend through the central hole of the work-piece, a forming-die mounted on said first-mentioned center and against which the work-piece is adapted to be rolled, said forming-die having an elongated hub portion into which the enlarged cylindrical portion of said center is slidably fitted, said bore being flared at its inner end to provide a hub-forming cavity of which the shoulder at the inner end of said enlarged cylindrical portion serves as the end wall, a side roll adapted to roll with its peripheral face against the side of the work-piece not engaged by said forming-die and in contact with its end face with said bored center, said side roll acting to force metal of the work-piece into the hub-forming cavity of said die, to roll the work-piece against the die for forming one side thereof to the shape of said die, and to roll said side of the work-piece not engaged by said die to desired shape.

129. In rolling mechanism, the combination of a forming-die adapted to have a work-piece rolled thereagainst and having a central bore, a work-supporting center having an enlarged portion slidable within said bore and a work-supporting portion extending inwardly from said enlarged portion, said work-supporting portion being adapted to be entered or forced into and extend through the central hole of the work-piece for supporting the latter, a second center alined with said first-mentioned center and adapted to have the end of the latter in slidable connection therewith, means for moving said centers axially together or independent of each other, a side roll adapted to roll against the work-piece at the side thereof not engaged by said die to force metal of the work-piece into the inner end portion of the bore of said forming-die and against the inner end of the enlarged cylindrical portion of the first-mentioned center, said roll being also adapted to reduce the thickness of the work-piece where desired and roll metal thereof outwardly beyond the peripheral edge of said die, and a peripheral face roll adapted to act against the peripheral face of said outwardly rolled portion of the metal and coacting with said side roll and said die to roll a rim portion on the work-piece.

130. In rolling mechanism, the combination of a pair of alined axially movable axles, centers detachably secured to said

- axles and by means of which a work-piece having a central hole is adapted to be supported, said centers being adapted to slidably fit one into the other and one of said centers being adapted to enter or forcibly enter and extend through the central hole of said work-piece, a forming-die on said last-mentioned center and against which a work-piece is adapted to be rolled, a pair of die-supporting rolls in rolling contact with said die, one of said die-supporting rolls having an edging roll part extending outwardly from the peripheral edge of said die, and an edging and web rolling roll adapted to roll against the work-piece at the side thereof not engaged by said die and to extend the work-piece outwardly over the peripheral edge of said die and against the edge rolling part of one of said die-supporting rolls, said side roll being also adapted to roll the work-piece at said side thereof not engaged by said die to form a web and a rim portion, a peripheral face rolling roll for rolling the outer peripheral face of said rim portion and being positioned between said edging roll part and said side roll and normally against the peripheral edge of said die, said face roll also determining the width of the rim portion when completed and being movable outwardly as the metal of the work-piece is extended by said side roll, a finishing roll adapted to roll said side or part of said side of the work-piece not engaged by said die to finish, and a peripheral face finishing roll between said finishing roll and the other die-supporting roll for rolling the peripheral face of the so formed rim to finish.
131. In an apparatus or mill for rolling or forming car wheels or other circular objects, the combination of a pair of aligned axially movable axles, centers secured to said axles by means of which a work-piece having a central hole is adapted to be supported, one of said centers having an axial bore and the other being adapted to extend through the central hole of the work-piece and enter said bore, a forming-die on said last-mentioned center against which die a work-piece is to be rolled, a pair of die-supporting rolls in rolling contact with said die at opposite sides of its axis, one of said rolls having an edging roll part extending outwardly from the peripheral edge of said die, an edging and web-rolling roll and a side finishing roll at the side of the work-piece not engaged by said die adapted to act against the work-piece, a peripheral face rolling roll and a peripheral face finishing roll adapted to act against the peripheral face of the work-piece, said peripheral face rolling roll coacting with said edging and web-rolling roll, the edging roll part of one of said die-supporting rolls and said die to roll or form the work-piece to rudiment

form, said peripheral face finishing roll coacting with said side finishing roll and said die to roll the rudimentarily formed work-piece to finish, and means for moving said axles and centers axially together in one direction independently of said rolls and said die.

132. In an apparatus or mill for rolling an ingot, bloom, blank or other work-pieces having a central hole into a car wheel or similar circular article having hub and rim portions extending from opposite sides of a web, the combination of a pair of axially movable aligned axles having work-supporting centers by means of which the work-piece is to be supported, said centers being adapted to telescope one within the other and one of said centers being adapted to extend through the central hole of the work-piece, a forming-die on one of said centers, and rolling rolls situated in a plane passing laterally through the work-piece and die and coacting with said die to roll or form the work-piece with opposite hub and rim portions and a web, and means for effecting relative movement of said centers and said rolls and die to dish the work-piece.

133. In an apparatus or mill for rolling or forming car wheels or other circular objects, a pair of aligned work-supporting axles having centers at adjacent ends by means of which a work-piece having a central hole is adapted to be positioned, one of said centers being adapted to extend into and through said hole and telescopically engage the other, a forming-die on one of said centers and in which said center is slidably arranged, said die being adapted to impart the shape thereof to one side of the work-piece including only the hub portion thereof, the web portion and the inner peripheral face of the rim portion at said one side of the work-piece, and rolls coacting with said die for rolling the remainder of the rim portion of the work-piece and the web and hub portion at the other side of the work-piece, including the end of said hub portion, and means for axially moving said centers together in one direction independently of said die and rolls.

134. In an apparatus or mill for rolling or forming car wheels or other circular objects, a pair of aligned axially movable axles having work-supporting centers at adjacent ends by means of which a work-piece having a central hole is adapted to be supported, one of said centers being cylindrical and having a flange at its inner end and having also a central bore, a forming-die on said center and having a bore of at least two different diameters to provide an inwardly facing shoulder against which the flange of said center is adapted to bear, the other center having a cylindrical or approximately cylindrical portion, a tapered por-

tion and a cylindrical end portion of smaller diameter than the adjacent end of said tapered portion, said cylindrical end portion being adapted to enter the bore of said first-mentioned center and providing a shoulder adapted to bear against the inner end of said first mentioned center, rolls coacting with said die to roll or form the work-piece to desired shape, and means for axially moving said axles together in one direction to cause the central portion of the work-pieces to be moved to dished position while retaining the marginal portion of the work-piece in fixed rotatable position by means 15 of said die and said rolls or of said die and at least one of said rolls.

135. In rolling mechanism, two coöperating spaced members between which a work-piece is to be rolled or formed, one 20 of said members being movable to approach the other or both of said members being movable to approach each other, one of said members being a forming-die and the other member having two rolling parts adapted 25 to roll one side of the work-piece to form two surfaces in different planes, the part of said other member rolling one of said surfaces determining the plane of the other surface.

136. In rolling mechanism, two coöperating spaced members between which a work-piece is to be rolled or formed, means 30 for effecting movement of one of said members toward the other or means for effecting movements of both of said members toward 35 each other, and means for governing said movement or movements, one of said members being a forming-die and the other member having two rolling parts of different 40 diameters, one of the rolling parts of said other member being adapted to engage said governing means and thereby regulate the rolling action of the other part.

137. In rolling mechanism, two coöperating spaced members between which a work-piece is to be rolled or formed, means for effecting movement of one of said members toward the other or means for effecting movements of both said members toward 50 each other, and means for governing said movement or movements, one of said members being a forming-die and the other member having three rolling parts to roll three different parts of the work-piece to at least 55 two different planes passing circumferentially through the work-piece, at least two of said three rolling parts having different diameters, one of said rolling parts being adapted to engage said governing means and 60 thereby regulate the rolling action of the other rolling parts against the work-piece.

138. In rolling mechanism, two coöperating spaced members between which a work-piece is to be rolled or formed and by means 65 of which the work-piece is to be rolled with

a web, a hub extending laterally in opposite directions and a rim also extending laterally in opposite directions from said web, one of said members being movable to approach the other or both said members being movable 70 to approach each other, one of said members being a rolling roll having three rolling parts and at least two of said three rolling parts having different diameters, one of said rolling parts being adapted to reduce 75 the thickness of the work-piece where desired to form said web and to roll metal outwardly to form said rim, the second rolling part of said roll being adapted to roll one end of said hub and the third rolling 80 part being adapted to roll one side of said rim, and a peripheral face rolling roll adapted to roll in contact with the periphery of the rim of the work-piece and against which said third rolling part rolls and is 85 limited in its movements, said third rolling part determining the final rolling positions of the remaining parts of said rolling roll.

139. In an apparatus or mill for rolling or forming car wheels or other circular objects, a pair of aligned work-supporting axles having means or being formed at adjacent ends thereof to engage a work-piece and between which means or ends a work-piece adapted to be rolled with a hub, a web and a 90 rim is to be positioned, a member at one side of the work-piece adapted to impart the desired form to the work-piece at said one side, a side roll at the other side of the work-piece coöperating with said member, and a face roll adapted to roll in contact with the peripheral face of the work-piece and to govern the movement of said side roll toward said member, said side roll having three rolling parts of at least two different 95 diameters to roll the web, one end of the hub and one side of the rim portion of the work-piece in at least two different planes. 100

140. In an apparatus or mill of the kind described, a pair of aligned work-supporting 110 axles having means or being formed at adjacent ends thereof to engage a work-piece and between which means or ends a work-piece is to be rolled or formed into a car-wheel or other circular article having a hub, a web and a rim is adapted to be supported or partly supported, a pair of forging members arranged at opposite sides of the work-piece, at least one of which members is adapted for rolling action against the work-piece and to act with the other member to roll or form opposite sides of the work-piece with hub portions, rim portions and an intervening web portion connecting said hub portions with said rim portions, said first-mentioned member having three rolling portions of at least two different diameters, and means for rolling the peripheral face of the work-piece and governing movement of said first-mentioned member toward the other 115 120 125 130

- member for determining the lateral thickness of the rim of the work-piece and in turn the thickness of the web and the length of the hub.
- 5 141. In rolling mechanism for rolling or forming a work-piece into a car wheel or the like having a hub, a web and a rim, the combination of a forming-die, a side roll between which and said forming-die a work-
10 piece is to be formed or rolled, and a face roll adapted to act against the peripheral face of the work-piece, said side roll having three rolling parts of three or at least two different diameters, one of said rolling parts
15 being adapted to roll in contact with said face roll to determine the lateral thickness of the marginal portion of the work-piece and thereby regulate the thickness of the web and the length of the hub formed by
20 the remaining rolling parts of said side roll.
142. An apparatus or mill of the kind described, comprising a pair of aligned work-supporting axles having means or being formed at adjacent ends thereof to engage a
25 work-piece and between which means or ends a work-piece is to be supported or partly supported, a forming-die arranged at one side of the work-piece and having a hub-forming cavity, a side roll at the other side
30 of the work-piece adapted to roll metal of the work-piece into said cavity to form a hub portion at said one side of the work-piece and to roll metal outwardly over the peripheral edge of the forming-die, said side roll being also adapted for rolling said
35 other side of the work-piece with a hub portion and having three rolling parts of at least two different diameters, one of said rolling parts being adapted to roll the end
40 face of the hub portion at said other side and the second rolling part being adapted to reduce the thickness of the metal around said hub portion and thereby form the web, said second rolling part being also adapted
45 to force metal laterally in opposite directions at the marginal portion of the work-piece, and a face roll adapted to act against the peripheral face of the work-piece and against which the third rolling part of said
50 side roll is also adapted to roll, said face roll being also adapted to govern the lateral width of the rim of the work-piece, the thickness of the web and the length of the hub of the work-piece.
- 55 143. In rolling mechanism for rolling or forming a work-piece into a car wheel or the like having a hub, a web and a rim portion, a forming-die, a side roll between which and said forming-die a work-piece is to be
60 formed or rolled, and a face roll adapted to roll against the peripheral face of the work-piece, said face roll having a lateral thickness equaling that which the rim portion of the work-piece is to have when finished, said
65 side roll having a hub-end rolling portion

of a given diameter, an edging roll portion of the same or of different diameter than said hub-end rolling portion adapted to roll the rim portion of the work-piece to desired lateral thickness and a web reducing or web 70 rolling portion of greater diameter than said edging roll portion adapted to roll the peripheral face of the hub portion, the inner peripheral face of said rim portion and the portion of the work-piece between said 75 hub portion and said rim portion, said face roll serving also as a stop-member and governing the lateral width of said rim portion, the length of said hub portion and the thickness of the metal between said rim and hub 80 portions.

144. In rolling mechanism for rolling or forming a work-piece into a car wheel or the like having a hub, a web and a rim, means for rotatably supporting a work-piece in a 85 fixed rotatable position, a side roll acting against one side of the work-piece, and a face roll adapted to act against the peripheral face of the work-piece, said side roll having three rolling parts of different diameters and being movable toward, against and into the work-piece to reduce the thickness of the work-piece between its central and marginal portion to form a hub, a web and a rim portion, one of said rolling parts being 90 adapted to engage and roll in contact with said face roll when said rim portion is rolled to desired lateral thickness, thereby limiting further lateral movement of said side roll and governing the length of said 95 hub portion and the thickness of said web portion.

145. In rolling mechanism, means for rotatably supporting a work-piece to be rolled with a hub portion, a web portion and a rim portion, a face roll adapted to act against the peripheral face of the work-piece and having a lateral thickness equaling that to which the rim portion of the work-piece is to be rolled, and a side roll having three rolling parts of at least two different diameters, one of said parts being adapted to roll in contact with said face roll to govern the lateral thickness of the rim portion of the work-piece, the length of the hub portion and the 110 thickness of the web portion.

146. An apparatus or mill of the kind described, comprising a pair of aligned rotatable axles having centers or piercers at adjacent ends between which a work-piece is 115 adapted to be supported, said centers or piercers having flanges and being adapted to pierce or penetrate the work-piece, a forming-die mounted on one of said centers or piercers and against which the work-piece 120 is to be rolled, said forming-die having a hub-forming cavity against the inner end wall of which the flange of said center or piercer bears, a side roll at the side of the work-piece not engaged by said die and 125 130

- adapted to be moved toward said die to force the work-piece thereagainst, to force metal of the work-piece around said centers or piercers and against the flanges thereof, to roll said work-piece so as to reduce the metal thereof where desired and form a web portion and to force metal of the work-piece outwardly beyond and over the peripheral edge of said forming-die, and a face roll adapted to act against the peripheral face of the metal extended outwardly by said side roll.
147. In rolling mechanism, two coöperating rolls, one a side roll adapted to act against one side of a work-piece and the other a face roll coöperating with said side roll and adapted to roll against the peripheral face of the work-piece, said face roll having a lateral thickness equaling that to which the rim portion of the work-piece is to be rolled, said side roll having two rolling portions rolling in contact with one of the side faces of said face roll.
148. In an apparatus or mill for rolling or forming car wheels or other circular objects, a pair of alined work-supporting axles, a forming-die supported by one of said axles and having a forming-face provided with a central hub-forming cavity and an annular rim-forming groove and having also a rim the inner face of which is adapted to form the peripheral face of a work-piece to the form of a flanged tread, a side roll normally spaced from said die and between which and said die the work-piece is to be positioned, said side roll being laterally and longitudinally movable and adapted to roll the work-piece into said die, said side roll being also adapted to roll in contact with the edge of the rim of said die during the final rolling operation.
149. In an apparatus or mill for rolling or forming car-wheels or other circular objects, a pair of alined work-supporting axles, a forming-die supported by one of said axles and having one side thereof provided with a depression whose inner wall and sides are adapted to form one side and the peripheral face of a work-piece, and a side roll movable toward and against said die and away from the same, said side roll being longitudinally movable and adapted to force the work-piece into said depression to reduce the thickness of the work-piece where desired and extend metal thereof outwardly against the sides of said depression, thereby forming one side and the peripheral face of the work-piece to the shape of said die, said side roll being also adapted to roll the face of the work-piece engaged thereby to desired shape.
150. In an apparatus or mill for rolling or forming car-wheels or other circular objects, a pair of alined rotatable and axially immovable axles having means or be-
- ing formed at adjacent ends thereof to engage a work-piece and between which means or ends a work-piece is to be supported, a forming-die coaxial with one of said axles and supported thereby, said forming-die being rotatable with said axle and having a depression whose inner wall is adapted to form one side of the work-piece and whose sides are adapted to form the peripheral face of the work-piece, a side roll or rolls to roll the side of the work-piece not engaged by said die to desired shape and to force the work-piece into the depression of said die, and means for moving said axles axially together in one direction independently of said die and said roll or rolls to dish the work-piece.
151. In an apparatus or mill for rolling or forming car-wheels or other circular objects, a pair of alined rotatable and axially movable supporting axles having means or being formed at adjacent ends thereof to engage a work-piece and between which means or ends a work-piece is adapted to be positioned, a forming-die carried by and coaxial with one of said axles, said forming-die being rotatable with said axle and having a depression in one side thereof whose inner wall is adapted to form one side of the work-piece and whose sides or surrounding wall is adapted to form the peripheral face of the work-piece, a longitudinally movable side roll having a web rolling part and an edging roll part of smaller diameter than said web rolling part, said web rolling part being adapted to be pressed or rolled into the metal of the work-piece at one side thereof and together with said edging roll part forcing the work-piece into the depression of said die and against the inner and surrounding walls thereof, said edging roll part being also adapted to roll in contact with the edge of said surrounding wall to limit the extent to which said web rolling part may be entered into the metal of said work-piece, thereby governing the thickness of the web portion of the work-piece, and means for moving said supporting axles axially together in one direction independently of said die and said roll to dish the work-piece.
152. In rolling mechanism, the combination of a forming-die having a depression in one side thereof whose inner wall is provided with a central hub-forming cavity and with an annular rim-forming groove, a side roll having two rolling parts of different diameters and being adapted to roll said work-piece into the depression of said die to form one side of the work-piece with a hub portion, a web portion, and a rim portion, the large rolling part of said side roll being adapted to be entered or forced into the metal to form the other side of the work-piece with a hub portion, a web por-

- tion and a rim portion, and the small part of said roll being adapted to roll the side of said last-mentioned rim portion and to roll against or in contact with the edge of the surrounding wall of said depression to govern the lateral thickness of the entire rim of the work-piece and the thickness of the entire web of the work-piece, and means for dishing the work-piece while the same is rotated and its marginal or peripheral portion supported and retained by said die and said side roll.
153. In rolling mechanism, the combination of a forming-die having a depression into which a work-piece is to be rolled, a longitudinally movable side roll adapted to roll the work-piece into said depression and to roll the side of the work-piece engaged thereby to desired form, and means for axially moving the hub or center portion of the work-piece while the same is rotated and its marginal or peripheral portion is supported and retained against said movement of said hub or center portion by said die and said roll.
154. In rolling mechanism, the combination of a pair of alined rotatable and longitudinally movable axles having means or being formed at adjacent ends thereof to centrally engage a work-piece from opposite sides thereof, and a forming-die carried by and coaxial with one of said axles, said forming-die being rotatable and longitudinally movable with said axle and having a forming-face against which the work-piece is adapted to be rolled.
155. In rolling mechanism, the combination of a forming-die having a depression in one of its sides provided with a surrounding wall and being formed to provide one side of the work-piece with a hub portion, a rim portion and a web portion and also to provide the peripheral face of the work-piece with a flange, and a longitudinally movable side roll adapted for movement toward and against said die and away from the same, said side roll having a web reducing roll part, a hub end-face roll part and an edging roll part, said edging roll part and web reducing roll part being adapted to force the work-piece into said die, said web reducing roll part being adapted to extend the work-piece outwardly against the surrounding wall of said depression and said hub end-face roll part being adapted to roll the end-face of the hub portion at the side of the work-piece engaged by said side roll, said edging roll part being also adapted during the final rolling operation to roll against or in contact with the edge of said surrounding wall to govern the length of the complete hub, the thickness of the web and the lateral thickness of the rim of the completed work-piece.
156. In rolling mechanism, the combination of a rotatably supported forming-die having a work-receiving depression formed in one side thereof and a longitudinal movable side roll having a hub-end rolling part, a web rolling part and an edging roll part and being adapted to roll a work-piece into said depression.
157. In an apparatus or mill for rolling or forming car wheels or other circular objects, the combination of a pair of alined work-supporting axles by means of which a work-piece is adapted to be supported, a rotatable forming-die coaxial with said axles and having a depression in one side thereof provided with a hub-forming cavity and an annular rim-forming groove, a longitudinally movable side roll co-operating with said die, to roll metal of the work-piece into said hub-forming cavity, into said annular rim-forming groove and against the surrounding wall of said depression, said side roll being also adapted to roll the side of the work-piece engaged thereby to form a hub portion, a web portion and a rim portion and a part of said roll being adapted to roll in contact with the edge of said surrounding wall to govern the length of the hub, the thickness of the web and the lateral thickness of the rim of the work-piece.
158. In rolling mechanism, the combination of a pair of alined and longitudinally movable axles, a forming-die mounted on and coaxial with one of said axles and having a forming-face against which a work-piece is to be rolled, said axles being longitudinally movable independently of said forming-die.
159. In rolling mechanism, the combination of a pair of alined and longitudinally movable axles, a forming-die supported by and coaxial with one of said axles and having a forming-face against which a work-piece is adapted to be rolled, and rolling means adapted to co-operate with said forming-die to roll or form the work-piece, said axles being longitudinally movable independently of said forming-die and said rolling means.
160. In rolling mechanism, the combination of a longitudinally movable axle, a forming-die supported by and coaxial with said axle and having a forming-face against which a work-piece is adapted to be rolled, said axle being longitudinally movable in either direction independently of said forming-die.
161. In rolling mechanism, the combination of a longitudinally movable axle, a forming-die mounted on and coaxial with said axle and having a forming-face against which a work-piece is adapted to be rolled, and rolling means adapted to co-operate with said forming-die to roll or form the work-piece, said axle being longitudinally mov-

able independently of said forming-die and said rolling means.

162. In rolling mechanism, the combination of a forming-die having a forming-face at one side thereof against which a work-piece is to be rolled, and having the other side thereof stepped to provide annular contact faces with outwardly facing shoulders, a stepped die-supporting roll having shoulders engaging said outwardly facing shoulders and rolling in contact with said contact faces, and rolling means adapted to cooperate with said forming-die to roll or form the work-piece to desired form.

163. In rolling mechanism, the combination of a forming-die having a work-receiving depression formed in one side thereof whose surrounding wall has its outer peripheral face adapted to support said die thereat, a pair of peripheral face supporting rolls adapted to roll against or in contact with the outer peripheral face of said surrounding wall, and rolling means adapted to cooperate with said forming-die to roll or form the work-piece as desired.

164. In rolling mechanism, the combination of a forming-die having a work-receiving depression formed in one side thereof and having a groove in its peripheral face, a pair of face rolls having peripheral flanges entered into said groove and supporting said die in both lateral and opposite radial directions, and a side roll or rolls adapted to roll a work-piece into said depression.

165. In rolling mechanism, the combination of a forming-die having a work-receiving depression formed in one side thereof whose surrounding wall has its outer peripheral face adapted to support said die thereat, a pair of die-supporting rolls in rolling contact with the other side of said die at opposite sides of its axis, a pair of peripheral face supporting rolls engaging the outer peripheral face of said surrounding wall at opposite sides of its axis, and a side roll or rolls adapted to roll a work-piece into said depression.

166. In rolling mechanism, the combination of a forming-die having a work-receiving depression formed in one side thereof and having a groove in its peripheral edge, a pair of die-supporting rolls rolling in contact with the opposite side of said die at opposite sides of its axis, a pair of face rolls having flanges entered into said groove, and a side roll or rolls adapted to roll a work-piece into said depression.

167. An apparatus or mill for rolling or forming car wheels or other circular objects, comprising a pair of alined rotatable work-supporting axles by means of which a work-piece is adapted to be supported, a forming-die supported by one of said axles and having a work-receiving depression formed in one side thereof, a side roll or

rolls adapted to roll the work-piece into said depression and to roll the side of the work-piece engaged thereby to desired form, and means for moving said axles together lengthwise while retaining the marginal portion of the rolled work-piece in fixed rotatable position.

168. An apparatus or mill for rolling or forming car wheels or other circular objects, comprising a pair of alined rotatable axles by means of which a work-piece is adapted to be axially supported, a forming-die rotatably supported and coaxial with said axles, said forming-die having a work-receiving depression formed in one side thereof, a longitudinally movable side roll adapted to roll a work-piece into said depression and to roll the side of the work-piece engaged thereby to desired form, a part of said roll being adapted to roll in contact with the marginal portion of said die during the final operation, and means for moving said axles together lengthwise while retaining the marginal portion of the rolled work-piece between said forming-die and said side roll.

169. An apparatus or mill for rolling or forming car wheels or other circular objects, comprising a pair of alined axles by means of which a work-piece is adapted to be axially supported, a forming-die supported by one of said axles, a side roll or rolls adapted to roll the work-piece into said die, and rolling supports engaging said die at its outer side and at its outer peripheral face.

170. An apparatus or mill for rolling or forming car wheels or other circular objects, comprising a pair of alined axles by means of which a work-piece is adapted to be axially supported, a rotatably supported forming-die through which one of said axles is axially passed, a side roll adapted to roll the work-piece into said die, and to rotate the work-piece with the said die, a second side roll spaced from said first-mentioned side roll and adapted to roll the side of the work-piece engaged thereby to finish, and means for moving said axles together lengthwise while retaining said side rolls in rolling engagement with the marginal portion of the work-piece.

171. An apparatus or mill for rolling or forming car wheels or other circular objects, comprising a pair of alined axles having telescoped work-supporting centers by means of which a work-piece is supported, one of said centers having an outwardly facing shoulder, a forming-die on said last-mentioned center and having a shouldered axial bore terminating at its inner end in a hub-forming or hub-receiving cavity of which said center forms the inner end wall, the shoulder of said axial bore being engaged by the shoulder of said center, rolling supports in rolling contact with the outer side of said forming-die at opposite sides

of its axis, a side roll or rolls adapted to roll a work-piece into said forming-die and to roll metal of the work-piece into said hub-forming cavity and against the end of said 5 last-mentioned center, and means of moving said axles together lengthwise while retaining the marginal portion of the work-piece in fixed rotatable position.

172. An apparatus or mill for rolling or 10 forming a work-piece having a central conical hole into the form of a car wheel or other circular article having a hub, a web and a rim, comprising a pair of alined axles having work-supporting centers at adjacent 15 ends, one of said centers having a tapered portion adapted to enter and extend through or be forced through the central conical hole of said work-piece and a reduced end portion forming a shoulder at the small end of 20 said tapered portion, the other center having a peripheral flange and an axial bore into which the reduced end portion of said first-mentioned center is entered, a forming-die having a work-receiving depression in 25 one side thereof of larger diameter than the work-piece to be rolled and having also a shouldered axial bore against which the flange of said second-mentioned center is adapted to bear, the inner end of said axial bore serving as a hub-forming cavity of 30 which said second-mentioned center forms the inner or end wall, means for rotatably supporting said forming-die at opposite sides of its axis, and a side roll having an 35 edging roll part and a web reducing or rolling part, said web reducing or rolling part being adapted to force metal of the work-piece into said hub-forming cavity to form the hub portion of the work-piece at one 40 side thereof and to roll the opposite side of the work-piece to desired form with a hub portion and extend metal outwardly against the surrounding wall of said depression.

173. An apparatus or mill for rolling or 45 forming car wheels or other circular objects, comprising a pair of alined work-supporting axles having work-supporting centers at adjacent ends, one of said centers having a reduced end portion and the other having 50 an axial bore to receive said end portion, said first-mentioned center being adapted to be entered or be forced into the central hole of the work-piece, a forming-die having a work-receiving depression formed in one 55 side thereof, means for rotatably supporting said die, a side roll adapted to roll the work-piece into said work-receiving depression, a second side roll adapted to roll in contact with the exposed or a portion of the 60 exposed side of the work-piece after or while being rolled by said first-mentioned side roll, and means for moving said centers together axially to dish the rolled or formed work-piece while rotating said work-piece 65 and said die with said side rolls and while

retaining the marginal portion of the work-piece against axial movement.

174. In an apparatus or mill for rolling or forming car wheels or other circular objects, the combination of a forming-die having a central hub-forming cavity and a depressed marginal portion provided with a circular outwardly-facing shoulder, a side roll or rolls spaced from said forming-die and between which and said forming-die a 70 work-piece is adapted to be rolled, and a pair of peripheral face rolls having one of their sides in contact with the depressed marginal portion of said die, one of said face rolls having a shouldered portion in 75 close proximity to or in contact with said outwardly facing shoulder and the other having a portion of its peripheral face in contact with said shoulder, said side roll or rolls being adapted to roll metal of the work-piece into said hub-forming cavity and 80 against the peripheral faces of said face rolls.

175. In an apparatus or mill for rolling or forming car wheels or other circular objects, the combination of a forming-die having a circular roll stop at its forming side, means for centrally and rotatably supporting a work-piece adapted to be positioned against said forming-die, a pair of opposite 90 peripheral face rolls, one of said face rolls being adapted for rolling in contact with said circular stop, and rolling means at the side of the work-piece not engaged by said forming-die for forcing the work-piece 95 against said die, extending metal of the work-piece outwardly against said peripheral face rolls and rolling the side of the work-piece engaged by said rolling means to desired form.

176. In an apparatus or mill for rolling or forming car-wheels or other circular objects, the combination of a forming-die having a circular roll stop at its forming side, means for centrally and rotatably supporting a work-piece adapted to be positioned against said forming-die, a pair of spaced 110 peripheral face rolls adapted to roll the peripheral face of the work-piece and being movable radially with respect to said die, 115 one of said face rolls being normally in proximity to or in contact with said circular stop and the other being in contact with said stop, and rolling means at the side of the work-piece not engaged by said die for forcing the work-piece against said die to form one side thereof to the shape of said die and for rolling the side of the work-piece not engaged by said die to desired 120 shape and extending the work-piece outwardly, one of said face rolls being movable with the changing diameters of said peripheral face.

177. In an apparatus or mill for rolling or forming car wheels or other circular objects,

the combination of a forming-die, a pair of peripheral face rolls having one of their sides in contact with the forming-side of said die, means for centrally supporting a work-piece with one side thereof against said forming-die, and rolling means at the opposite side of the work-piece for rolling the work-piece against said die and against said face rolls and also for rolling said opposite side to desired form.

178. In an apparatus or mill for rolling or forming car wheels or other circular objects, the combination of a forming-die having a circular outwardly facing shoulder at 5 its forming side and having the region within the said shoulder formed to provide one side of a work-piece with a hub portion, a rim portion and a depressed portion between said hub and rim portions, a pair of peripheral face rolls having one of their sides in contact with the forming of said die, means for centrally and rotatably supporting a work-piece with one side thereof against said forming-die, and rolling means at the other 15 side of the work-piece for rolling the same against the said die, for rolling said other side with a hub portion and a depressed intermediate portion and also for extending the work-piece radially against said face 20 rolls or against one of said face rolls and rolling a rim portion on said opposite side, one of said face rolls being movable outwardly while the work-piece is being extended radially and both face rolls being 25 adapted to roll against the peripheral face of the extended or rim portion of the work-piece to roll the peripheral face thereof as desired.

179. In an apparatus or mill for rolling or forming car wheels or other circular objects, the combination of a pair of aligned work-supporting axles having piercers or centers at adjacent ends by means of which a work-piece is adapted to be supported, a 40 forming-die on one of said piercers or centers against which the work-piece is to be rolled, said forming-die having a circular outwardly facing shoulder at its forming-side, a pair of peripheral face rolls having 45 one of their sides in contact with the forming-side of said die, means for rolling the side of the work-piece not engaged by said die to form one side of the work-piece to the shape of said die and to roll the other side 50 thereof to desired shape and also to extend the work-piece radially against said face rolls, and means for moving said axles together longitudinally while the work-piece is rotating and while retaining the rim portion 55 of the work-piece in fixed rotatable position between said rolling means, said face rolls, and said die.

180. An apparatus or mill for rolling or forming car wheels or other circular objects, 60 comprising forming or rolling mechanism,

and centering or piercing mechanism by means of which latter a work-piece is adapted to be rotatably supported, said forming or rolling mechanism including a forming-die having a circular roll stop, a pair of peripheral face rolls, one of said face rolls being adapted for rolling in contact with said stop, and a pair of side rolls at opposite sides of the axis of the work-piece for rolling the latter with the coöperation of the 70 said die and face rolls to the form of a car wheel or other circular object having a hub, a web and a rim, said rolling mechanism and centering or piercing mechanism being relatively movable parallel or practically 80 parallel to the axis or extended axis of the work-piece to dish the latter.

181. An apparatus or mill for rolling or forming car-wheels or other circular objects, comprising a pair of telescoping rotatable 85 axially movable work-supporting centers by means of which a work-piece is to be supported, a rotatable forming-die against which the work-piece is to be rolled, said forming-die having a forming-face provided 90 with a circular raised portion formed with a central hub-forming cavity and with a marginal portion and being coaxial with said centers, a pair of peripheral face rolls having one of their sides in contact with the 95 marginal portion at the forming-side of said die, and a pair of side rolls engaging the side of the work-piece not engaged by said forming-die, at least one of said rolls being adapted to force metal of the work-piece 100 into said hub-forming cavity, to force metal of the work-piece outwardly over the peripheral edge of said circular raised portion and against said face rolls or against one of said face rolls and also to roll the side of 105 the work-piece not engaged by said die to form a hub portion, a rim portion and an intermediate depressed or web portion, said other side roll being adapted to roll the inner periphery of said rim portion to finished form, one of said peripheral face rolls being movable with the changing diameters 110 of the outer peripheral face of the work-piece and both face rolls being adapted to roll said peripheral face.

182. An apparatus or mill for rolling or forming car wheels or other circular objects, comprising means for centrally and rotatably supporting a work-piece, a rotatable forming-die coaxial with said supporting 115 means, a pair of face rolls coöoperating with the peripheral edge of said forming-die and arranged at opposite sides of the axis of the work-piece, a pair of side rolls also arranged at opposite sides of the axis of the 120 work-piece and between which and said die a work-piece is to be positioned, one of said side rolls coöoperating with one of said face rolls and said forming-die to roll the marginal portion of the work-piece into a rudi- 125 130

mentarily formed rim and the other side roll coöperating with the other face roll and said forming-die to roll the rudimentarily formed rim to finished form.

- 5 183. An apparatus or mill for rolling or forming car wheels or other circular objects, comprising means for centrally and rotatably supporting a work-piece, a rotatable forming-die coaxial with said supporting means and against which the work-piece is adapted to be positioned, a pair of die-supporting rolls in rolling contact with the outer side of said forming-die, one of said die-supporting rolls having an edging roll 10 part extending outwardly from the peripheral edge of said die, a pair of peripheral face rolls arranged at opposite sides of the axis of the work-piece, a pair of side rolls arranged at the side of the work-piece not engaged by the forming-die and at opposite sides of the axis of the work-piece, one of the side rolls coöperating with one of said face rolls with the edging roll part of said die-supporting roll and with said die to roll 15 or form the marginal portion of the work-piece into a rudimentarily formed rim, the other side roll coöperating with the other face roll and with said forming-die to roll or form the rudimentarily formed rim to 20 finished form.
184. In an apparatus or mill for rolling or forming car wheels or other circular objects, the combination of a pair of alined rotatable work-supporting axles having piercers 25 or centers at adjacent ends adapted to axially pierce, penetrate or center a work-piece, a forming-die on one of said piercers or centers, a pair of peripheral face rolls at opposite sides of the axis of the work-piece 30 coöperating with the peripheral edge of said forming-die, a side roll positioned with its end in contact with the peripheral face of one of said piercers or centers and having an edging roll part and a web reducing part, 35 said side roll being adapted to roll the work-piece against said forming-die and to roll the side of the work-piece engaged thereby to a hub portion and reduce the thickness of the work-piece adjacent said hub portion to 40 form the inner portion of the web, and a second side roll at the opposite side of said last-mentioned piercer or center adapted to roll the work-piece to form the outer portion 45 of the web and the inner peripheral face of the rim portion.

185. In an apparatus or mill for rolling or forming car wheels or other circular objects, the combination of rotatable work-supporting means for axially supporting a work-piece, a rotatable forming-die coaxial with said work-supporting means and against which a work-piece is to be rolled, a pair of peripheral face rolls at opposite sides of the axis of the work-piece coöperating with 55 the peripheral edge of said forming-die, a

pair of side rolls adapted to roll in contact with the side of the work-piece not engaged by said forming-die, one of said side rolls rolling the work-piece against said die to form one side thereof to the shape of said die 70 and to roll the other side thereof to a hub portion and reduce the metal of the work-piece adjacent the hub portion to form the inner portion of the web and also to extend the work-piece radially against one of said 75 face rolls, the other side roll rolling the work-piece to form the outer portion of the web and the inner peripheral surface of the rim.

186. An apparatus or mill for rolling or forming car wheels or other circular objects, comprising a pair of alined work-supporting axles having piercers or centers at adjacent ends to axially pierce or penetrate or center and support a work-piece, 85 one of said piercers or centers having a tapered end portion and a cylindrical or approximately cylindrical portion adjacent said tapered portion and the other piercer or center having a flange providing inwardly and outwardly facing shoulders, a tapered end portion at one side of said flange and a cylindrical portion at the other side of said flange, a forming-die against which the work-piece is to be rolled, said 90 forming die having a central bore provided with an inwardly facing shoulder engaging the outwardly facing shoulder of said flange and being flared inwardly from the inner end of said flange to provide an annular intervening space between the wall of said flared portion and the tapered end portion of said last-mentioned piercer or center, a pair of peripheral face rolls co-operating with the peripheral edge of said 100 die, and a side roll adapted for rolling action against the side of the work-piece not engaged by said die and having a hub end-face rolling portion, an edging roll portion of the same or of different diameter than 105 said hub end-face rolling portion and a web rolling or reducing portion of larger diameter than said edging roll portion, said side roll having its end in contact with the cylindrical or approximately cylindrical 110 portion of said first-mentioned piercer or center and being adapted to roll metal of the work-piece into said hub-forming cavity, extend the work-piece radially over the peripheral edge of the forming-die and 115 against one of said face rolls, whereby one side of the work-piece is provided with a hub portion, a rim portion and a depressed intermediate portion, said side roll also rolling the other side of the work-piece 120 with a hub portion, a rim portion and a depressed intermediate portion.

187. In an apparatus or mill for rolling or forming car-wheels or other circular objects, a rotatably supported forming-die 130

- having a forming-face against which a work-piece is to be rolled, rolling means for rolling the work-piece against said forming-face to form one side of the work-piece to the shape of said forming-face including the forming of the side of the marginal or rim portion or extended marginal or rim portion of the work-piece at said side and for rolling the other side of the work-piece to desired shape including the rolling of the side of said marginal or rim portion at said other side, and rolling means for rolling the peripheral face of the work-piece to desired shape.
15. 188. In an apparatus or mill for rolling or forming car-wheels or other circular objects, a rotatably supported forming-die having a forming-face whose outer peripheral edge is of a diameter which is the same as the diameter which the inner peripheral face of the marginal or rim portion of the work-piece at its side next to said forming-face is to have when finished and against which forming-face the work-piece is to be rolled, rolling means for rolling the work-piece against said forming-face to form the portion of the work-piece or extended portion of the work-piece at one side thereof inside of said marginal or rim portion to the shape of said forming-face and for rolling the other side of the work-piece to desired shape including the rolling of the side of said marginal or rim portion at said other side, rolling means for rolling the side of said marginal or rim portion of the work-piece at the side of the work-piece next to said forming-face, and rolling means for rolling the peripheral face of the work-piece first to rudimentary shape and then to finished shape.
20. 191. In an apparatus or mill for rolling or forming car-wheels or other circular objects, a rotatably supported forming-die having a forming-face against which a work-piece is to be rolled, rolling means for rolling the work-piece against said forming-face to form one side of the work-piece to the undished shape of said forming-face and for rolling the other side of the work-piece to desired undished shape, rolling means for rolling the peripheral face of the work-piece to desired shape, and means for dishing the work-piece while said marginal or rim portion of the work-piece is kept in contact with said die and both of said rolling means or with said die and at least said first-mentioned rolling means.
25. 192. In an apparatus or mill for rolling or forming car-wheels or other circular objects, a rotatably supported forming-die having a forming-face whose outer peripheral edge is of a diameter which is the same as the diameter which the inner peripheral face of the marginal or rim portion or extended marginal or rim portion of the work-piece at its side next to said forming-face is to have when finished and against which forming-face the work-piece is to be rolled, rolling means for rolling the work-piece against said forming-face to form the portion or extended portion of the work-piece at one side thereof inside of said marginal or rim portion to the undished shape of said forming-face and for rolling the other side of the work-piece to desired undished shape including the rolling of the side of said marginal or rim portion at said other side, rolling means for rolling the side of said marginal or rim portion at the side of the work-piece next to said forming-face, and rolling means for rolling the peripheral face of the work-piece to desired shape.
30. 190. In an apparatus or mill for rolling or forming car-wheels or other circular objects, a rotatably supported forming-die having a forming-face whose outer peripheral edge is of a diameter which is the same as the diameter which the inner peripheral face of the marginal or rim portion or ex-

said die and both of said rolling means or with said die and at least said first-mentioned rolling means.

193. In an apparatus or mill for rolling or forming car-wheels or other circular objects, a forming-die having a forming-face against which a work-piece is to be rolled, rolling means for rolling the work-piece against said forming-face to form one side 10 of the work-piece to the undished shape of said forming-face and for rolling the other side of the work-piece to desired undished shape, rolling means for rolling the peripheral face of the work-piece first to rudimentary shape and then to finished shape, and means for dishing the work-piece before or during or after the rolling of said peripheral face.

194. In an apparatus or mill for rolling or forming car-wheels or other circular objects, a forming-die having a forming-face whose outer peripheral edge is of a diameter which is the same as the diameter which the inner peripheral face of the marginal 25 or rim portion or extended marginal or rim portion of the work-piece at its side next to said forming-face is to have when finished and against which forming-face the work-piece is to be rolled, rolling means 30 for rolling the work-piece against said forming-face to form the portion or extended portion of the work-piece at one side thereof inside of said marginal or rim portion to the undished shape of said forming-face and for rolling the other side of the 35 work-piece to desired undished shape including the rolling of the side of said marginal or rim portion at said other side, rolling means for rolling the side of said marginal or rim portion at the side thereof 40 next to said forming-face, rolling means for rolling the peripheral face of the work-piece first to rudimentary shape and then to finished shape, and means for dishing the work-piece before or during or after the rolling of said peripheral face.

195. An apparatus or mill for rolling or forming car-wheels or other circular objects, comprising a pair of aligned longitudinally movable work-supporting axles by means of which a work-piece is to be axially supported, a rotatable forming-die coaxial with said axles, and rolls coöperating with said forming-die, all combined to roll or form a work-piece into a car wheel or other circular object having a hub, a web and a rim, and to dish the car wheel or other object after being so rolled or formed.

196. In an apparatus or mill for rolling or forming car-wheels or other circular objects, a forming-die against which a work-piece is to be rolled and having a forming-face adapted to form a central portion at one side of the work-piece or extended 65 work-piece, rolling means adapted to co-

operate with said forming-face for rolling the side of the work-piece not engaged by said forming-face, for pressing or rolling the work-piece against said forming-face so as to form the central portion at the 70 other side of the work-piece to the shape of said forming-face, for rolling the remainder of said other side extending beyond said central portion and for rolling the peripheral face of the work-piece.

197. In an apparatus or mill of the kind described for rolling a work-piece having a central hole into the form of a car wheel, the combination of a pair of aligned rotatable work-supporting axles, a center secured to the inner end of one of said axles and adapted to enter said central hole from one side of the work-piece, a forming-die mounted on the inner end of the other axle and having a forming-face and a centering 85 projection extending from said forming-face and adapted to enter the central hole from the other side of the work-piece, and rolls coöperating with said die to roll or form the work-piece to desired shape.

198. In an apparatus or mill of the kind described for rolling a work-piece into the form of a car wheel or other circular object, the combination of a pair of aligned rotatable work-supporting axles, a center secured to the inner end of one of said axles and adapted to bear axially against one side of the work-piece, a forming-die mounted on the inner end of the other axle and having a forming-face and a pin or 100 pins extending from said forming-face and adapted to be forced into the work-piece at the other side thereof, and rolls coöperating with said die to roll or form the work-piece to desired form.

199. In an apparatus or mill of the kind described for rolling a work-piece having a central hole tapered inwardly from opposite sides into the form of a car wheel or other circular object having a hub and a laterally reduced portion surrounding said hub, the combination of a pair of aligned rotatable axles, a tapered piercer or center secured to the inner end of one of said axles and adapted to enter or be forced into said central hole from one side of the work-piece, a forming-die at the other side of the work-piece mounted on the inner end of the other axle and having a forming-face provided with a central hub-forming cavity having 115 an axial tapered piercing or centering portion integral therewith and adapted to enter or be forced into said central hole from the other side of the work-piece, and rolls coöperating with said die to roll or form the work-piece to desired shape.

200. An apparatus or mill for rolling or forming car-wheels or other circular objects, comprising means for centrally and rotatably supporting a work-piece, a rota-

- table forming-die coaxial with said supporting means and having a conical peripheral edge, a side roll between which and said forming-die a work-piece is to be positioned, said side roll operating against one side of the work-piece to cause the other side thereof to be shaped to the form of said die to cause metal of the work-piece to be extended outwardly and over the peripheral edge of said die and thereby form a rim portion having its inner peripheral face formed sufficiently inclined by the conical edge of said die to cause compression of the metal in said rim portion, said side roll having an enlarged portion provided with a conical rolling face whereby a rim portion is formed at the first-mentioned side of the work-piece and whereby the inner peripheral face thereof is rolled sufficiently conical to cause compression of metal in said rim portion, and a face roll acting against the peripheral face of the work-piece and with said side roll and forming-die rolling the rim of the work-piece to uniform or practically uniform density.
201. An apparatus or mill for rolling or forming car wheels or other circular objects, comprising means for centrally and rotatably supporting a work-piece, a rotatable forming-die coaxial with said supporting means, said die having a conical peripheral edge, a die-supporting roll rolling in contact with the outer side of said die and having an edging roll part extending outwardly from the conical peripheral edge of said die, a side roll between which and said forming-die a work-piece is to be positioned, said side roll being adapted to roll said work-piece against said forming-die and to cause metal of the work-piece to be extended outwardly over the conical peripheral edge of said die and thereby form a rim portion on the die side of the work-piece having its inner peripheral face formed sufficiently inclined to cause compression of the metal in said rim portion, said side roll having an enlarged rolling portion provided with a conical rolling face whereby a rim portion is formed on the roll side of the work-piece and whereby the inner peripheral face of said rim portion is rolled sufficiently inclined to cause compression of metal in said rim portion, a face roll adapted to act against the peripheral face of the work-piece and with said side roll, the edging roll part of said die-supporting roll and the peripheral edge of said forming-die roll or form the metal in the rim of the work-piece to uniform density, a second side roll at the roll side of the work-piece spaced from said first-mentioned side roll, and a second face roll adapted to act against the peripheral face of the work-piece and with said second mentioned side roll and the peripheral edge of said forming-die roll or

form the inner peripheral face of said last mentioned rim portion and the outer peripheral face of the entire rim of the work-piece to finished form and to roll the metal in the entire rim of the work-piece to maximum or approximately maximum density.

202. An apparatus or mill for rolling or forming car wheels or other circular objects, comprising a rotatable forming-die, a pair of die-supporting rolls engaging the outer side of said die, each of said die-supporting rolls having a straight faced roll part extending outwardly beyond the peripheral edge of said die, a pair of peripheral face rolls, and a pair of side rolls in the same lateral plane as said die-supporting rolls adapted to act against one of the sides of a work-piece, at least one of said side rolls being adapted to roll the work-piece against said forming-die, over the peripheral edge thereof and against the edging roll part of the supporting roll opposite said side roll and also against the peripheral face of the face roll between said two last mentioned rolls.

203. An apparatus or mill for rolling or forming car wheels or other circular objects, comprising a pair of aligned work-supporting heads arranged for longitudinal movement, a longitudinally movable rotatable axle within each head movable therewith, said axles being aligned and having piercers or centers at adjacent ends by means of which a work-piece is to be supported, a forming-die mounted on one of said centers to permit said center, its axle and supporting head to move lengthwise independent of said die, and rolls cooperating with said die to roll the work-piece to desired form.

204. An apparatus or mill for rolling or forming car wheels or other circular objects, comprising a pair of aligned longitudinally movable work-supporting heads, aligned axles rotatable within said heads and longitudinally movable therewith, piercers or centers at adjacent ends of said axles by means of which a work-piece is to be supported, a forming-die coaxial with said piercers or centers against which the work-piece is to be rolled and in which one of said piercers or centers is slidably arranged, a side roll or rolls acting against the work-piece at the side thereof not engaged by said forming-die, and a face roll or rolls adapted to roll against the peripheral edge of the work-piece, and piercers or centers with their axles and work-supporting heads being movable lengthwise together for dishing the work-piece while retaining the marginal portion of the work-piece in fixed rotatable position by means of said die and rolls or by means of said die and said side roll or rolls.

205. An apparatus or mill for rolling or forming car wheels or other circular objects,

- comprising a pair of alined work-supporting axles having piercers or centers at adjacent ends of unequal lengths, said piercers or centers being adapted to axially pierce or penetrate a work-piece from opposite sides to unequal depths, a forming-die mounted on one of said piercers or centers and against which the work-piece is to be rolled, and a side roll or rollers adapted to roll against the side of the work-piece not engaged by said forming-die to roll the work-piece against said die, to reduce the thickness of the metal of the work-piece where desired to form a web, to roll or form a hub at the inner or central region of said web and to form or roll a rim at the outer region thereof, said hub having the center of its length out of alinement with said web to position the same to conform to the position of the hub of a dished car wheel.
206. An apparatus or mill for rolling or forming car wheels or other circular objects, comprising a pair of alined rotatable work-supporting axles, piercers or centers secured to adjacent ends of said axles, one of said centers being provided with a longitudinal keyway, a forming-die against which a work-piece is to be rolled, said forming die being rotatable with said center and having a keyway in opposition to the keyway of said center, a key fitted into said keyways for causing said center to rotate with said forming-die, or vice-versa, while permitting said center to slide within said die, a side roll or rolls for acting against the side of the work-piece not engaged by said forming-die to roll the work-piece against said die and to extend the work-piece outwardly over the peripheral edge of said die, and face rolls adapted to roll against the peripheral face of the work-piece and roll the rim or marginal portion of the work-piece to desired form with the assistance of said side roll or rolls and said forming die.
207. An apparatus or mill for rolling or forming car wheels or other circular objects, comprising a pair of alined work-supporting axles, piercers or centers at adjacent ends of said axles between which a work-piece is to be positioned, a forming-die rotatable with and slidable on one of said piercers or centers, and means for rotating and rolling a work-piece against said die to roll the work-piece including the rolling of the peripheral face thereof to desired form and cause rotation of said die with said work-piece.
208. In an apparatus or mill for rolling or forming car-wheels or other circular objects, a forming-die having a forming-face against which a work-piece is to be rolled, said forming-die being adapted to form a central portion of the work-piece at the die-side thereof or at the side thereof engaged by said forming-die during the operating process, rolling means adapted to coöperate with said forming-die for rolling the other side or the side of the work-piece not engaged by said forming-die to desired shape and for pressing or rolling the work-piece against said forming-face so as to form said central portion at the die-side of the work-piece to the shape of said forming-die, for rolling the remainder of said die-side of the work-piece extending beyond said central portion and for rolling the peripheral face of the work-piece, and means for dishing the work-piece before or during or after the rolling of said peripheral face.
209. An apparatus or mill for rolling or forming car-wheels or other circular objects, comprising a pair of alined rotatable work-supporting axles, a center secured to one of said axles and provided with hub-supporting means, a forming-die secured to the other axle and having a hub entering or hub forming cavity and a center surrounded by said cavity, and rolls coöoperating with said forming-die to roll or form or upset the marginal or rim portion of the work-piece to smaller diameter while rolling or forming the inner peripheral face or faces and while rolling the outer peripheral face of said marginal or rim portion and also while rolling against or in contact with the opposite sides of said marginal or rim portion.
210. In an apparatus or mill for rolling or forming car-wheels or other circular objects, a forming-die having a forming-face against which a work piece is to be rolled and being adapted to form a central portion at one side of the work-piece during the operating process, rolling means adapted to coöperate with said forming-die for rolling the other side or the side of the work-piece not engaged by said forming-die to desired shape and for pressing or rolling the work-piece against said forming-die so as to form said central portion at the die-side of the work-piece to the shape of said forming-die, for rolling the remainder of said die-side of the work-piece extending beyond said central portion and for rolling the peripheral face of the work-piece, and means for dishing the work-piece before or during or after the rolling of said peripheral face, said rolling means being also adapted to roll said peripheral face and the marginal or rim portion or a portion thereof of the work-piece after the work-piece has been dished.
211. An apparatus or mill for rolling or forming car wheels or other circular objects, comprising a pair of alined rotatable work-supporting axles, a center secured to one of said axles and having a tapered centering portion and a rim or flange spaced from said centering portion and provided with a flared inner hub-compressing wall,

said centering portion being adapted to enter the bore of a work-piece from one side thereof and said rim or flange being adapted to surround the hub of the work-piece and 5 compress the same to reduce the diameter of said bore at one end thereof, a forming-die secured to the other work-supporting axle and having a hub-receiving cavity provided with a flaring side wall and a tapered centering portion arranged axially within said hub-receiving cavity and adapted to enter the bore of said work-piece from the other side thereof, said flaring side wall of said cavity engaging the peripheral face of the 10 hub at the same side of work-piece and compressing the same to reduce the diameter of said bore at the other end thereof, rolls co-operating with said forming-die to roll the work-piece as desired, and means for moving 15 said work-supporting axles lengthwise.

212. An apparatus or mill for rolling or forming car wheels or other circular objects, comprising a pair of aligned longitudinally movable rotatable work-supporting 25 axles, one of said axles having a piercer or center provided with an outstanding flange, a forming-die secured to the other work-supporting axle and having an integral piercer or center shorter than said first- 30 mentioned piercer or center and extending axially from the forming-face of said die, said forming-die having a diameter equaling that or less than that which the rolled work-piece is to have when completed, a 35 pair of face rolls adapted to be positioned with their peripheral faces in line with the peripheral edge of the work-piece, one of said face rolls having a lateral width equaling that which the outer portion of the 40 work-piece is to have when finished, a conical side roll spaced from said forming-die and adapted for rolling contact with said last-mentioned face roll, and a second side roll adapted to roll the work-piece to cause 45 one side thereof to be shaped to the form of said die and to cause metal of the work-piece to be rolled toward said piercers or centers and against the outstanding flange of said first-mentioned piercer or center, 50 said second side roll being movable radially with respect to the work-piece and having a straight-faced portion in rolling contact with the other face roll, said last-mentioned face roll being movable outwardly away 55 from the peripheral edge of the work-piece with the outward movement of said second side roll.

213. An apparatus or mill for rolling or forming car wheels or other circular objects, 60 comprising a pair of aligned longitudinally movable rotatable work-supporting axles, a piercer or center secured to one of said axles and adapted to pierce or penetrate the work-piece from one side thereof, a forming-die secured to the other work-supporting

axle and having a forming-face at one side thereof and a piercer or center extending axially from said forming-face and adapted to pierce or penetrate the work-piece from the other side thereof, die-supporting rolls 70 rolling in contact with said forming-die at the other side thereof and having straight-faced portions extending outwardly from the peripheral edge of said die, a pair of opposite peripheral face rolls against one of 75 the sides of which the straight-faced portions of said die-supporting rolls are adapted to roll, one of said face rolls having a lateral width equaling that which the marginal portion of the work-piece is to have 80 when finished, a straight-faced side roll adapted to roll against the other side of said last-mentioned face roll and against the work-piece, and a second side roll adapted to act against the work-piece to roll the 85 same to desired form preparatory to said first-mentioned side roll acting against said work-piece, said second side roll having a straight-faced portion rolling against the other side of the other face roll, said second 90 side roll and said last-mentioned face roll being movable together to permit said face roll to be moved away from the peripheral edge of the work-piece when moving said side roll outwardly.

214. An apparatus or mill for rolling or forming car wheels or other circular objects, comprising a pair of aligned work-supporting axles between which a work-piece is to be positioned, a forming-die supported by 100 one of said axles and having a flat forming-face at one side thereof provided with a central hub-forming cavity, said forming-die having its other side stepped and having a diameter equaling or smaller than that 105 which the diameter of the work-piece is to be when finished, a pair of stepped die-supporting rolls rolling in contact with the stepped side of said die and having straight rolling portions whose peripheral faces are 110 in line with the flat forming face of said die, a pair of opposite peripheral face rolls, one of said face rolls having a lateral width equaling that which the outer portion of the work-piece is to have when finished, a 115 side roll having a straight peripheral faced portion in rolling contact with the side of the other face roll and a second rolling portion adapted to roll metal of the work-piece into the central hub-forming cavity of said 120 die to form a hub portion at one side of the work-piece, to roll metal inwardly at the other side of the work-piece to form a hub portion thereon and to reduce the thickness 125 of the metal around said hub portions and extend metal of the work-piece outwardly to a diameter conforming to that of said forming-die, said side roll being movable radially with respect to the work-piece and said face roll being outwardly movable 130

away from the peripheral face of the work-piece, and a second side roll having a straight-faced rolling portion in contact with said first-mentioned face roll and in 5 rolling contact with the work-piece of a portion of the work-piece rolled by said first-mentioned side roll.

215. An apparatus or mill for rolling or forming car wheels or other circular objects, comprising a pair of aligned longitudinally movable rotatable work-supporting axles, piercers or centers secured to adjacent ends of said axles and adapted to axially pierce or penetrate a work-piece from opposite sides, said piercers or centers being of unequal lengths and having shoulders limiting the piercing or penetrating action thereof so that the work-piece is pierced or penetrated from opposite sides to unequal 15 depths, a forming-die, and rolls co-operating with said forming-die to roll or form the work-piece with a hub, a web and a rim, all combined to operate so that said web is formed central with respect to the rim but 20 out of center with respect to length of the hub.

216. An apparatus or mill for rolling or forming car wheels or other circular objects, comprising means for centrally supporting 30 a work-piece, a forming-die having an inner forming-face, an outer marginal supporting face, and an oppositely beveled peripheral edge, the inner bevel of said edge rounding into the inner surface of said 35 forming-face, a pair of die-supporting rolls having their axes parallel with or inclined to the outer marginal supporting face of said die and each having two rolling portions forming an inwardly-facing shoulder 40 in contact with the outer bevel of the edge of said die, a pair of peripheral face rolls, and a side roll adapted to roll the work-piece against said forming-die and with said face rolls being adapted to roll the 45 work-piece to desired form, one of the two rolling portions of each die-supporting roll rolling in contact with the side of one of said face rolls and the other rolling portion of each die-supporting roll rolling in contact 50 with the marginal supporting face of said die.

217. In an apparatus or mill for rolling or forming car wheels or other circular objects, the combination of a pair of aligned 55 work-supporting heads, a pair of axially aligned rotatable work-supporting axles mounted in said heads, piercers or centers at adjacent ends of said axles by means of which a work-piece is to be supported, a 60 forming-die carried by one of said axles, spaced die supporting and edge rolling rolls mounted on one of said work-supporting heads and each having a portion thereof in rolling contact with said forming-die and 65 the other portion thereof extending out-

wardly from the peripheral edge of said die and adapted to roll in contact with the marginal or rim portion of the work-piece at the side thereof next to said die, rolls co-operating with said forming-die and said die 70 supporting and edge rolling rolls to roll or form the work-piece to desired form, and means for moving said axles lengthwise together for dishing the work-piece while retaining the marginal portion of the work-piece in fixed rotatable position by means of said forming-die and said rolls. 75

218. In an apparatus or mill for rolling or forming car wheels or other circular objects, the combination of a pair of aligned 80 work-supporting heads, a pair of axially aligned work-supporting axles rotatable within said heads, piercers or centers secured to adjacent ends of said axles by means of which a work-piece is to be supported, a 85 forming die carried by one of said axles or by one of said piercers or centers, a plurality of spaced die supporting and edge rolling rolls carried by one of said supporting heads and each having a portion thereof in rolling contact with the marginal portion of said die at its outer side and the other portion thereof extending outwardly from the peripheral edge of said die, the outwardly extending portion of at least one of said supporting and edge rolling rolls being adapted 90 to roll in contact with the side of the marginal or rim portion of the work-piece at the side thereof next to said die, and rolling means co-operating with said forming-die 95 and said die-supporting and edge rolling rolls for rolling the work-piece to desired 100 form including the rolling of the peripheral face thereof.

219. In an apparatus or mill for rolling 105 or forming car wheels or other circular objects, the combination of a pair of aligned work-supporting heads, a pair of axially aligned work-supporting axles rotatable within said heads, a forming-die carried by and 110 coaxial with one of said axles, spaced brackets secured to one of said supporting heads, rolls within said brackets in rolling contact with the marginal portion of said die, and side and face rolls co-operating with said 115 forming-die to roll the work-piece to finished form with a hub, a web and rim.

220. In an apparatus or mill for rolling or forming car wheels or other circular objects, the combination of a pair of aligned 120 work-supporting axles, piercers or centers secured to adjacent ends of said axles and adapted to axially center, pierce or penetrate a work-piece from opposite sides, a forming-die in which one of said piercers 125 or centers is slidably arranged, a plurality of supporting rolls retained in fixed rotatable positions and spaced equi-distantly against the outer side of the marginal portion of said forming-die, said last mentioned 130

5 piercer or center being adapted to slide axially in said forming-die, rolls coöperating with said forming-die to roll the work-piece into the form of a car wheel or other object having a hub, a web and a rim, and means for moving said axles with their piercers or centers axially together for dishing the car wheel or other object thus rolled or formed while retaining the marginal portion 10 of said car wheel or other object in fixed rotatable position by means of said forming-die and rolls.

221. In an apparatus or mill for rolling or forming car wheels or other circular objects, the combination of a pair of alined work-supporting heads, a work-supporting axle rotatably mounted in each of said heads, power or pressure mechanism connected to at least one of said work-supporting heads for moving the same longitudinally, power or pressure mechanism connected to the axle within said work-supporting head, means for connecting said axle with or disconnecting the same from said work-supporting head so that it may be moved with said head or within said head independently thereof, piercers or centers secured to adjacent ends of said axles by means of which a work-piece is to be supported, a forming-die coaxial with said piercers or centers, and rolls coöperating with said forming-die to roll or form the work-piece to desired form.

222. In an apparatus or mill for rolling or forming car wheels, or other circular objects, the combination of a pair of alined longitudinally movable work-supporting heads, axles rotatable within said heads, piercers or centers secured to adjacent ends 40 of said axles by means of which a work-piece is to be supported, means for moving said axles longitudinally together in one direction independent of said work-supporting heads or with said work-supporting heads, and means for forming the work-piece supported by said piercers or centers to desired form.

223. In an apparatus or mill for rolling or forming car wheels or other circular objects, the combination of a pair of alined longitudinally movable work-supporting heads, axles rotatable within said heads, piercers or centers secured to adjacent ends of said axles by means of which a work-piece is to be supported, means for moving said work-supporting heads longitudinally, means for connecting said axles to and disconnecting the same from said work-supporting heads to cause them to be moved longitudinally with said heads or permit them to move longitudinally independent of said heads, means for moving said axles longitudinally while retaining said work-supporting heads in fixed positions, and means

for rolling or forming the work-piece to 65 desired shape.

224. In an apparatus or mill for rolling or forming car wheels or other circular objects, the combination of a pair of alined work-supporting heads, a pair of alined longitudinally movable axles rotatable within said heads, a constant power or pressure device connected with one of said work-supporting heads, means for connecting the axle of said work-supporting head to said head or disconnecting said axle therefrom, a constant power or pressure device connected with said axle and being adapted to move the same longitudinally, means for controlling said power or pressure devices whereby 80 either may be operated at will, piercers or centers secured to adjacent ends of said axles by means of which a work-piece is to be supported, means for rolling or forming the work-piece to desired shape and for retaining the marginal portion of the work-piece when dishing the same by the longitudinal movement of said axle within its supporting head, and means for permitting the coöperating axle to recede with the 90 movement of said first-mentioned action.

225. In an apparatus or mill for rolling or forming car wheels or other circular objects, the combination of a pair of alined work-supporting heads, a constant power or 95 pressure device connected with one of said heads for moving the same longitudinally toward and from the other, a pair of axially alined longitudinally movable rotatable axles within said heads, a constant power or pressure device connected with one of said axles for moving the same longitudinally within its supporting head, piercers or centers secured to adjacent ends of said axles between which a work-piece is to be supported, means 100 for regulating the extent of movement of said supporting head, means for regulating the extent of longitudinal movement of said axle independent of its supporting head, means whereby the other axle is permitted 105 to move lengthwise with said first-mentioned axle, and rolling or forming elements adapted to operate against the work-piece and to retain the marginal portion of the work-piece in fixed rotatable position while 110 moving said axles together lengthwise for dishing the work-piece.

226. An apparatus or mill for rolling or forming car wheels or other circular objects, comprising opposite supports, axially alined work-supporting axles rotatable within said supports, piercers or centers secured to adjacent ends of said axles by means of which a work-piece is to be supported, detachable means for causing movement of said supports lengthwise with said axles and when detached permitting movement of said axles lengthwise independent of said supports,

- and means for rolling or forming the work-piece into the form of a car wheel or other circular object having a hub, a web and a rim and whereby the rim of the work-piece 5 may be retained in fixed rotatable position when moving said axles together lengthwise with said supports or independent of said supports for dishing the work-piece.
227. An apparatus or mill for rolling or 10 forming car wheels or other circular objects, comprising spaced supports, axially alined work-supporting axles rotatable within said supports, piercers or centers secured to adjacent ends of said axles by means of which 15 a work-piece is to be supported, means for moving one of said supports lengthwise, means for connecting the axle of said support with or disconnecting the same from said support, means for moving said axle 20 lengthwise independent of its support, a forming-die carried by said axle or by the piercer or center of said axle and against which forming-die the work-piece is to be rolled, rolls coöoperating with said forming-die to roll or form the work-piece to desired 25 form, and means whereby the other axle is permitted to move lengthwise with said first mentioned axle to permit of dishing the work-piece while retaining the marginal portion 30 of the latter in fixed rotatable position by means of said die and rolls.
228. An apparatus or mill for rolling or 35 forming car wheels or other circular objects, comprising spaced supports, axially alined work-supporting axles rotatable within said supports, piercers or centers secured to adjacent ends of said axles by means of which a work-piece is to be supported, a forming-die mounted on one of said piercers or sup- 40 porting centers and in which said piercer or center is arranged for slidable movement, spaced supporting rolls carried by one of said supporting heads and in rolling contact with the marginal portion of said forming- 45 die, power or pressure means for moving said supports lengthwise toward or from each other, power or pressure mechanism for moving said axles and the piercers or centers thereof lengthwise together or inde- 50 pendent of each other, means for connecting one of said axles to its support to compel said axle to be moved lengthwise with said support, and means for rolling or forming the work-piece to desired form.
229. An apparatus or mill for rolling or 55 forming car wheels or other circular objects, comprising two alined work-supporting heads, work-supporting axles rotatable within said heads and axially alined for supporting a work-piece therebetween, power or pressure mechanisms connected to said heads and axles to permit of moving said heads lengthwise with their axles or for moving said axles lengthwise together or independ- 60 ent of each other within said heads, and 65 means for retaining the marginal portion of the work-piece in fixed rotatable position while moving said axles lengthwise together for dishing the work-piece.
230. In an apparatus or mill for rolling or 70 forming car wheels or other circular objects, the combination of two alined work-supporting heads, work-supporting axles rotatable within said heads and axially alined for supporting a work- 75 piece therebetween, a power or pressure device for each of said axles comprising a cylinder, a piston within said cylinder and a piston-rod extending through said cylinder from opposite ends, one end of each 80 piston-rod being connected to its coöperating work-supporting axle to cause said axle to move with said rod, means on each of said rods for limiting the movement thereof in opposite directions, a second power 85 or pressure device for each of said work-supporting heads comprising a cylinder, a piston within said cylinder and a piston-rod extending through said cylinder from opposite ends and having one end thereof connected to its coöperating work-supporting 90 head to cause said head to move with said rod; means on each said last-mentioned piston-rod for limiting the movement thereof in opposite directions, means for disconnect- 95 ing each of said first-mentioned piston-rods from its coöperating work-supporting axle whereby said axles may be moved with their supporting heads, means for rolling or forming the work-piece to desired form and for 100 retaining the marginal or rim portion of the work-piece in fixed rotatable position when operating said first-mentioned power or pres- 105 sure devices for moving said axles longitudinally together in one direction and causing the work-piece to be dished.
231. In an apparatus or mill for rolling or 110 forming car wheels or other circular objects, the combination of two pairs of power or pressure devices, each pressure device comprising a pressure cylinder, a piston and a piston-rod extending from opposite ends of said piston and projecting through oppo- 115 site ends of said pressure cylinder, a pair of work-supporting heads, each head having the piston-rod of one of each pair of said power or pressure devices connected thereto to cause lengthwise movement thereof, alined axles rotatable within said heads and each having connection with the piston-rod of the other of each pair of power or pres- 120 sure devices to cause longitudinal movement of said axle independent of its supporting head, piercers or centers secured to adjacent ends of said axles to axially center, pierce or penetrate a work-piece, means for rolling or forming the work-piece to desired form and for retaining the marginal or rim por- 125

tion of the work-piece in fixed rotatable position while the power or pressure devices operatively connected with said axles cause the latter to be moved longitudinally together in one direction for dishing the work-piece.

232. In an apparatus or mill for rolling or forming car wheels or other circular objects, the combination of a pair of aligned work-supporting heads having adjacent ends spaced apart, a pair of rotatable axially aligned axles within said heads, a power or pressure device for each of said work-supporting heads for moving said heads lengthwise including a longitudinally movable element connected to said supporting head and having adjustable stops adapted to engage fixed parts of the apparatus for regulating the movement of said work-supporting head, power or pressure devices for moving said work-supporting axles longitudinally together or independent of each other within said heads, each of said last-mentioned power or pressure devices including a longitudinally movable element connected to one of said axles and having adjustable stops adapted to engage fixed parts of the apparatus for regulating the movement of said axle, piercers or centers secured to adjacent ends of said axles for axially supporting a work-piece, and means for rolling or forming the work-piece to desired form and for retaining the marginal or rim portion of the work-piece in fixed rotatable position while moving said axles together by means of their coöperating power or pressure devices for dishing the work-piece.

233. In an apparatus or mill for rolling or forming car wheels or other circular objects, the combination with work-positioning mechanism, of a pair of aligned work-supporting heads, a pair of axially aligned work-supporting axles rotatable within said heads, piercers or centers secured to adjacent ends of said axles by means of which the work-piece is to be axially supported, means for moving said work-supporting heads lengthwise, means for connecting said axles to said heads to cause said axles to move lengthwise with said heads, means for limiting the movements of said heads with said axles to determine the working positions of said piercers or centers against or within the work-piece, means for disconnecting said axles from said heads after the working positions of said piercers or centers are determined, means for moving said work-supporting axles with their piercers or centers lengthwise together or independent of each other and independent of said heads, and means for rolling or forming the work-piece into the form of a car wheel or other circular object having a hub, a web and a rim and whereby the marginal portion of said work-piece is retained in fixed rotatable po-

sition while moving said work-supporting axles axially together independent of said heads for dishing the car wheels.

234. An apparatus or mill for rolling or forming car wheels or other circular objects, comprising a pair of aligned work-supporting heads, a power or pressure device for each work-supporting head operatively connected therewith for moving said head longitudinally, work-supporting axles rotatable within said heads and axially aligned for supporting a work-piece therebetween, and a power or pressure device surmounting one or each of said first-mentioned power or pressure devices, one or each of said surmounted power or pressure devices being operatively connected with one of said work-supporting axles for moving the same longitudinally, and means for rolling or forming the work-piece to desired form. 85

235. An apparatus or mill for rolling or forming car wheels or other circular objects, comprising a pair of aligned work-supporting heads, a power or pressure device operatively connected with each of said work-supporting heads for moving the same longitudinally, work-supporting axles rotatable within said heads and axially aligned for supporting a work-piece therebetween, a power or pressure device surmounting one or each of said first-mentioned power or pressure devices, said surmounted power or pressure device or each of said surmounted power or pressure devices being operatively connected with one of said work-supporting axles for moving the same longitudinally and including a longitudinally movable rod having an adjustable stop to govern the extent of approaching movement of its work-supporting axle and to govern the receding movement of its work-supporting head, and means for rolling or forming the work-piece to desired form. 90 95 100

236. An apparatus or mill for rolling or forming car-wheels or other circular objects, comprising a pair of aligned work-supporting heads, a power or pressure device operatively connected with each of said work-supporting heads for moving the same longitudinally toward or away from each other and for maintaining the same under constant pressure when so moved, axially aligned work-supporting axles rotatable within said heads and having means or being formed at adjacent ends thereof to engage a work-piece therebetween, a power or pressure device surmounting one or each of said first-mentioned power or pressure devices, said surmounted power or pressure device or each of said surmounted power or pressure devices being operatively connected with its work-supporting axle for moving the same longitudinally toward the other work-supporting axle or toward each other to engage and rotatably support a work- 110 115 120 125 130

piece therebetween and to maintain said axle or axles under constant pressure when supporting the work-piece, said surmounted power or pressure device or each of said 5 surmounted power or pressure devices including a longitudinally movable rod having an adjustable stop to respectively govern the extent of longitudinal movement of its work-supporting head and its work-supporting axle, and means for rolling or forming the work-piece to desired form and for retaining the marginal portion of the work-piece in a fixed rotatable position when rolled or formed, said adjustable stop or 10 stops being adapted to strike a fixed part or parts of the apparatus or mill when moving the work-supporting axles together for dishing the work-piece while retaining the marginal portion of the work-piece in fixed 15 rotatable position, thus governing the extent to which the work-piece is to be dished.

237. An apparatus or mill for rolling or forming car wheels or other circular objects, comprising a pair of aligned work-supporting heads, power or pressure devices operatively connected with said work-supporting heads for moving the same longitudinally including means for regulating the range of movements of said heads, axially aligned work-supporting axles rotatable within said heads, piercers or centers secured to adjacent ends of said axles between which a work-piece is to be supported, a power or pressure device operatively connected with one or each of said work-supporting axles for moving the same longitudinally including means for regulating the range of movements of said axle or axles, a forming-die mounted on one of said 30 piercers or centers, a die-supporting roll or rolls in rolling contact with the outer side of said forming-die, a side roll or roll adapted to roll the work-piece against and over the peripheral edge of said forming-die to cause one side of the work-piece to be formed to the shape of said die and to roll the other side of the work-piece to desired form, and a peripheral face roll or rolls 35 cooperating with said forming-die and said side roll or rolls to roll the rim portion of the work-piece with a flanged tread, said die and rolls retaining the marginal or rim portion of the work-piece in fixed rotatable position while moving said work-supporting axles longitudinally together for dishing the work-piece.

238. An apparatus or mill for rolling or forming car-wheels or other circular objects, comprising a pair of aligned work-supporting heads, a power or pressure device operatively connected with each of said work-supporting heads for moving the same longitudinally including means for regulating the range of movements of said heads, axially aligned work-supporting axles rotatable

within said heads, one of said axles being adapted to move with its head and the other being adapted to be moved independently of its head, piercers or centers secured to adjacent ends of said axles between which a work-piece is to be supported, a power or pressure device operatively connected with the work-supporting axle which is movable independently of its head for moving said axle longitudinally including means for regulating the range of movements of said axle, a forming-die slidably mounted on the piercer or center of said last-mentioned axle and against which a work-piece is to be rolled, a pair of die-supporting rolls in rolling contact with said forming-die at opposite sides of its axis, said die-supporting rolls being carried by the work-supporting head of said independently movable axle, opposite peripheral face rolls adapted to roll the peripheral face of the work-piece, a side roll adapted to roll the side of the work-piece not engaged by said forming-die to cause the work-piece at one side thereof to be formed to the shape of said die and to roll the other side of the work-piece to desired form and to extend the work-piece outwardly over the peripheral edge of said forming-die and against said face rolls or one of said face rolls, and a second side roll adapted to roll the marginal portion of the so formed work-piece at the side thereof not engaged by said die, said die and rolls retaining the marginal or rim portion of the work-piece in fixed rotatable position while moving said work-supporting axles longitudinally together with the power or pressure device connected with one of said axles for dishing the work-piece.

239. In an apparatus or mill for rolling or forming car-wheels or other circular objects, a work-supporting head having a chambered end portion, a longitudinally movable work-supporting axle rotatable within said head and having a flange thereon within said chambered end portion, a thrust bearing inside said chambered end portion and retaining in contact with the flange of said axle to move lengthwise therewith, guiding means connected to said head for guiding the inner end or inner end part of said axle, operating rods connected to said thrust bearing and also guided for movement in said guiding means, a cross-head to which corresponding outer ends of said operating rods are connected, and power or pressure means connected with said cross-head.

240. In an apparatus or mill for rolling or forming car-wheels or other circular objects, a work-supporting head having a chambered portion at one end, an end plate closing the end of said chambered portion, a plurality of guide rods secured to said end of said supporting head and passing through

125

130

said end plate, said guide rods extending from said supporting head, a guide plate connected to the projecting outer ends of said guide rods, a longitudinally movable 5 rotatable work-supporting axle extending through said supporting head and journaled therein and in said end plate, said axle having a peripheral flange in the chambered end portion of said head, a thrust bearing 10 rounding said axle and retained in contact with said peripheral flange to move with said axle, operating rods guided in said guide plate and in said end plate and having their inner ends fastened to said thrust bearing, a cross head connected to the outer ends 15 of said operating rods, and power or pressure mechanism connected with said cross-heads whereby said axle is moved longitudinally within said work-supporting head 20 through the medium of said operating rods.

241. In an apparatus or mill for rolling or forming car-wheels or other circular objects, a work-supporting head having an enlarged inner end hollowed out to form a chamber, 25 an end plate closing said chamber, bearings in said supporting head, a bearing in said end plate, a longitudinally movable rotatable work-supporting axle journaled in the bearings of said supporting head and having 30 a peripheral flange within the chamber of said head, a retainer sleeve secured to said axle to rotate and move lengthwise therewith, a thrust bearing between said flange and said retainer sleeve, said sleeve being 35 journaled in the bearing of said end plate and having its one end in contact with said thrust bearing, a guide member spaced from said end plate and supported from said supporting head, said guide member also serving 40 to slidably support the adjacent end or end part of said axle, operating rods guided for longitudinal movement within said guide member and within said end plate, said operating rods extending through said 45 end plate and being connected to said thrust bearing, a cross-head connected to the outer ends of said operating rods, and a power or pressure device having a piston-rod connected to said cross-head.

50 242. In an apparatus or mill for rolling or forming car-wheels or other circular objects, a work-supporting head having an enlarged inner end hollowed out to form a chamber, an end plate closing said chamber, 55 a ball thrust bearing within said chamber, a longitudinally movable rotatable work-supporting axle journaled in said work-supporting head and extending through said thrust bearing, said axle having a peripheral flange lying in contact with said thrust bearing and being also reduced in diameter outwardly from said thrust bearing to provide two spaced opposed shoulders, a two-part retainer sleeve secured to 60 said axle between said shoulders to rotate 65

and move longitudinally with said axle, a bearing in said end plate in which said two part sleeve is journaled, a guide member spaced from said end plate and receiving support from the inner end of said supporting head, longitudinally movable operating rods guided within said guide member and said end plate and having their inner ends reduced to form shoulders, said ends being secured within one of the parts 70 of said thrust bearing and having shoulders bearing against the outer face of said part, and means for moving said operating rods longitudinally whereby said work-supporting axle is similarly moved within said 75 supporting head.

243. In an apparatus or mill for rolling or forming car-wheels or other circular objects, a work-supporting head having an enlarged inner end hollowed out to form a chamber, an end plate adapted to close said chamber, a plurality of rods passed through the marginal portion of said end plate and threaded into the inner end of said head, nuts threaded onto said rods and bearing 80 against said end plate to fasten the latter against said head, said rods extending outwardly, a distance from said end plate, a guide member secured to the outer ends of 85 said rods, a longitudinally movable rotatable work-supporting axle journaled in said work-supporting head and having a peripheral flange within the chamber of said head, a multi-part sleeve journaled in said end plate and being rotatable and longitudinally movable with said axle, a ball 90 thrust bearing between said flange and said multi-part sleeve, said sleeve surrounding said axle and bearing with one end against said thrust bearing, a plurality of operating 95 rods secured at their inner ends to said thrust bearing and guided for longitudinal movement within said guide member and said end plate, means connecting the outer ends of said operating rods together, 100 and an operating device secured to said connecting means whereby said work-supporting axle, said multi-part sleeve, said operating rods and said thrust bearing are 105 caused to move lengthwise.

244. In an apparatus or mill for rolling or forming car wheels or other circular objects, a work-supporting head having an enlarged inner end hollowed out to form a chamber, an end plate secured to the inner end of 110 said head to close said chamber, a longitudinally movable work-supporting axle rotatable within said head and having a peripheral flange within said chamber spaced from said end plate, a thrust bearing within 115 said chamber comprising a non-rotatable part adapted for longitudinal movement with said axle and a rotatable part adapted to rotate with said axle, and operating rods connected to the non-rotatable part of said 120 125 130

thrust bearing and being slidable within said end plates.

245. In an apparatus or mill for rolling or forming car wheels or other circular objects, a work-supporting head having an enlarged portion at its inner end hollowed out to form a chamber and having a bearing or bearings in the part thereof extending outwardly from said enlarged portion, a rotatable and longitudinally movable work-supporting axle journaled in said bearing or bearings and extending inwardly and outwardly therefrom, a work-supporting center or piercer detachably secured to the outer end of said axle, said axle having a peripheral flange within said chamber and a reduced portion spaced from said flange and providing two spaced opposing shoulders, a multi-part retainer sleeve fitting within said reduced portion and having the parts thereof bearing with opposite ends against said shoulders, an end plate secured to the inner end of said supporting head to close the chamber thereof and having a bearing therein in which said retainer sleeve is journaled, an anti-friction thrust bearing within said chamber between the adjacent end of said retainer sleeve and the flange of said axle comprising a non-rotatable part adapted for longitudinal movement with said axle, a part in contact with the flange of said axle and rotatable therewith and anti-friction elements interposed between the two parts of said bearing, operating rods extending through said end plate and having their inner ends fastened to the non-rotatable part of said thrust bearing, means for guiding the outer portions of said operating rods, and means for moving said operating rods lengthwise to cause longitudinal movement of said work-supporting axle.

246. In an apparatus or mill for rolling or forming car wheels or other circular objects, a work-supporting head having a chambered inner end, a rotatable and longitudinally movable axle within said supporting head, operating rods having connection to said axle within said chambered inner end to cause longitudinal movement of said axle but permit independent rotary movement of the same, said operating rods being slidable within the inner end wall of said head, and means whereby said operating rods may be connected to said head for causing said axle to move with said head.

247. In an apparatus or mill for rolling or forming car wheels or other circular objects, a work-supporting head having an enlarged portion at its inner end hollowed out to form a chamber, a longitudinally movable and rotatable work-supporting axle within said head, operating rods guided for movement within the inner end wall of said chamber and having key-holes therein at points outside of said inner end wall, said

operating rods being connected within said chamber to said axle to cause the latter to move longitudinally with said operating rods but permit independent rotary movement thereof, and keys adapted to be inserted in said key holes and bear against the outer face of said inner end wall to cause said axle to be moved with said supporting head. 70

248. In an apparatus or mill for rolling or forming car wheels or other circular objects, a work-supporting head having an enlarged inner end portion hollowed out to form a chamber, an end plate closing the inner end of said chamber, means for moving said work-supporting head longitudinally, a work-supporting axle rotatable within said work-supporting head, operating rods extending through said end plate and connected within said chamber to said axle to cause longitudinal movement of said axle but permit independent rotary movement of the same, said operating rods being slidable within said end plate, means for moving said operating rods lengthwise whereby said axle may be moved longitudinally within said head, and means for locking said operating rods against slidable movement within said end plate whereby said axle is caused to move lengthwise with said head when moving the latter. 80 90 95

249. In an apparatus or mill for rolling or forming car wheels or other circular objects, the combination of a supporting head, an axle rotatable within said supporting head, operating rods connected to said axle for moving the same lengthwise within said supporting head, a guide member receiving support from the inner end of said supporting head, and means for internally cooling said axle including a cooling medium inlet member connected to the inner end of said axle and a sliding or supporting portion extending from said inlet member and guided for movement within said guide member. 100 105 110

250. In an apparatus or mill for rolling or forming car wheels or other circular objects, the combination of a work-supporting head having a chambered inner end, a hollow axle rotatable and slidable within said work-supporting head, a plurality of operating rods slidable within the inner end wall of said work-supporting head and having connection at their inner ends to said axle 120 in a manner to permit the latter to rotate but to cause the same to slide with said rods, a guide-member spaced from the inner end of said work-supporting head and receiving support from said supporting head, said 115 125 operating rods being slidable within said guide member, a sleeve surrounding the inner end of said axle and having an annular chamber surrounding said axle and an outlet pipe connected to said chamber, said 130

- sleeve being packed at opposite ends around said axle, said axle having an opening or port placing the interior thereof in communication with said annular chamber, a 5 tube having one end entered into the inner end of said axle, a pipe extending lengthwise within said axle and having one end connected with one end of said tube, said pipe being open at its other end and being 10 separated from the wall of said axle by an intervening space, and a cooling medium inlet member connected to the other end of said tube and having a guide portion extending axially therefrom, said guide portion being guided for slidable movement 15 within said guide member.
251. In an apparatus or mill for rolling or forming car wheels or other circular objects, the combination of a work-supporting 20 head having a chambered inner end, a hollow axle rotatable and slidable within said work-supporting head, said axle having its outer end closed and its inner end open and being provided with an outlet port or ports 25 near its inner end, a plurality of operating rods slidable within the inner end wall of said work-supporting head and having connection at their inner ends to said axle to cause the latter to slide with said rods but 30 permit said axle to rotate independent of said rods, a guide-member spaced from the inner end of said work-supporting head and in which said operating rods are slidably retained, a sleeve surrounding the inner end 35 of said axle and having an annular chamber connected by means of said outlet port or ports with the interior of said axle, said sleeve being packed at one end, a tube arranged within the inner end of said axle 40 and having a portion thereof reduced in diameter to form a shoulder and the outer end of said reduced portion threaded, a pipe rigidly secured with one end thereof to the inner end of said tube and extending 45 lengthwise within said axle, said pipe being separated from the surrounding wall of said axle by an annular intervening space, and having its other end spaced from the outer end wall of said axle, a packing member 50 at the outer end of said sleeve to pack the latter and being also adapted to pack said tube at the inner end of said axle, and a cooling medium inlet chamber into one end of which the threaded end of the reduced 55 portion of said tube is entered, said inlet member having an axial guide portion extending therefrom and guided in said guide member.
252. In an apparatus or mill for rolling 60 or forming car-wheels or other circular objects, a rotatably supported forming-die having a forming-face against which a work-piece is to be rolled and which forming face is adapted to form a central portion 65 at one side of the work-piece during the op-

erating process, rolling means adapted to coöperate with said forming-face for rolling the side of the work-piece not engaged by said forming-face and for pressing or rolling the work-piece against said forming-face for forming the first-mentioned side of said central portion to the shape of said forming-face, for rolling the remainder of said first-mentioned side of the work-piece extending beyond said central portion and for rolling the peripheral face of the work-piece first to rudimentary shape and then to finished shape, and means for dishing the work-piece before or during or after the rolling of said peripheral face. 7

253. In an apparatus or mill for rolling or forming car-wheels or other circular objects, a rotatably supported forming-die having a forming-face against which a work-piece is to be rolled and which forming-face is adapted to form a central portion at one side of the work-piece during the operating process, rolling means adapted to coöperate with said forming-face for rolling the side of the work-piece not engaged by said forming-face, for pressing or rolling the work-piece against said forming-face for forming said central portion at the first-mentioned side of the work-piece to the shape of said forming-face, for rolling the remainder of said first-mentioned side of the work-piece extending beyond said central portion and for rolling the peripheral face of the work-piece first to rudimentary shape and then to finished shape, and means for dishing the work-piece before or during or after the rolling of said peripheral face. 8

254. An apparatus or mill for rolling or forming car-wheels or other circular objects, comprising a rotatably supported forming-die having a forming-face at one side thereof against which a work-piece is to be rolled, a pair of spaced peripheral face rolls adapted for rolling or forming the peripheral face of the work-piece, a pair of die-supporting and edge rolling rolls, the die-supporting portion of said last-mentioned rolls being adapted to roll in contact with the other side of said die and the edge rolling portion of one of said rolls extending outwardly from the peripheral edge of said forming-face and being adapted to roll in contact with the side of the marginal or rim portion of the work-piece extending over the peripheral edge of said forming-face and also to roll in contact with a portion of one of the sides of one of said face rolls, the edge rolling portion of the other of said rolls extending outwardly from the peripheral edge of said forming-face and 11

over said side of said marginal or rim portion and being adapted to roll in contact with one of the sides of the other of said face rolls, and a pair of side rolls between which and said forming-face the central portion of the work-piece is to be rolled or formed, a portion of one of said side rolls being adapted to roll in contact with the other side of said marginal or rim portion and with a portion of the other side of said first-mentioned face roll and a portion of the other of said side rolls being adapted to roll in contact with a portion of the other side of the other of said face rolls, all combined to roll or form the work-piece into a car-wheel or other circular object having a hub, a web and a rim.

255. In rolling mechanism for rolling or forming car-wheels or other circular objects, a forming-die against which a work-piece is to be rolled, rolls coöoperating with said die to roll or form the work-piece to desired undished form, and means for disting the work-piece before or during or after the rolling or forming of the peripheral face of the work-piece.

256. An apparatus or mill for rolling or forming car-wheels or other circular objects, comprising a rotatably supported forming-die having a forming-face at one side thereof against which a work-piece is to be rolled, a pair of spaced peripheral face rolls adapted for rolling or forming the peripheral face of the work-piece, a pair of die-supporting and edge rolling rolls, the die-supporting portion of said last-mentioned rolls being adapted to roll in contact with the other side of said die and the edge rolling portion of one of said rolls extending outwardly from the peripheral edge of said forming-die and being adapted to roll in contact with the side of the marginal or rim portion of the work-piece extending over the peripheral edge of said forming-face and also to roll in contact with a portion of one of the sides of one of said face rolls, the edge rolling portion of the other of said rolls extending outwardly from the peripheral edge of said forming-face and over said side of said marginal or rim portion and being adapted to roll in contact with one of the sides of the other of said face rolls, a pair of side rolls between which and said forming-face the central portion of the work-piece is to be rolled or formed, a portion of one of said side rolls being adapted to roll in contact with the other side of said marginal or rim portion and with a portion of the other side of said first-mentioned face roll and a portion of the other of said side rolls being adapted to roll in contact with a portion of the other side of the other of said face rolls, all combined to roll or form the work-piece into an undished car-wheel or other circular object having a

hub, a web and a rim, and means for effecting dishing of the work-piece or car-wheel or other object.

257. In rolling mechanism for rolling or forming car-wheels or other circular objects, a rotatable forming-die having a forming-face at one side thereof against which a work-piece is to be rolled and a supporting face or faces and gear or driving teeth at its other side, a roll or a portion of a roll in rolling contact with said supporting face or faces to support said die thereat and being formed or provided with a toothed gear meshing with said gear or driving teeth.

258. In rolling mechanism for rolling or forming car-wheels or other circular objects, a rotatable forming-die having a forming-face at one side thereof against which a work-piece is to be rolled and having a supporting face or faces and gear or driving teeth at its other side, and rolls at different points of and in rolling contact with said supporting face or faces to support said die thereat, at least one of said rolls being formed or provided with a toothed gear meshing with said gear or driving teeth and having also a portion of said roll extending outwardly from the peripheral edge of said forming-face and adapted to roll against or in contact with the side of the work-piece extending over said peripheral edge.

259. In rolling mechanism for rolling or forming car-wheels or other circular objects, a peripheral face roll or rolls adapted for rolling or forming the peripheral face of a work-piece, a rotatable forming-die having a forming-face at one side thereof against which the work-piece is to be rolled and a supporting face or faces and gear or driving teeth at its other side, and rolls at different points of and in rolling contact with said supporting face or faces to support said side thereat, at least one of said last-mentioned rolls being formed or provided with a toothed gear meshing with said gear or driving teeth, a portion of said roll extending outwardly from the peripheral edge of said forming-face and being adapted to roll against or in contact with the side of the work-piece extending over said peripheral edge and also with a portion of one of the opposite sides of one of said face rolls.

260. The method of rolling or forming car-wheels or other circular objects from heated ingots, blooms, blanks or other work-pieces, which consists in positioning a work-piece against the forming-face of a die having a diameter corresponding to that which the inner peripheral face of the marginal or rim portion of the car-wheel or other object is to have at the side thereof next to said die, in subjecting the work-piece at the side thereof not engaged by said forming-die and in subjecting the marginal or rim portion of

the work-piece extending outwardly from the peripheral edge of said die at the side of the work-piece next to said die to the action of side rolls for rolling said side not engaged by said die to desired shape while forcing the work-piece against and over the forming-face of said die and, for rolling the side of said marginal or rim portion of the work-piece at the side thereof next to 5 said forming-die, and in subjecting the peripheral face of the work-piece to the rolling action of a face roll or rolls while rolling the opposite sides of the marginal or rim portion of the work-piece with said first- 10 mentioned side rolls.

261. The method of rolling or forming car-wheels or other similar objects having each a laterally extending rim or marginal portion from heated ingots, blooms, blanks, 20 or other work-pieces, which consists in positioning the work-piece against the forming-face of a die having a diameter equaling that which the inner peripheral face of the laterally extending rim or marginal portion 25 of the work-piece is to have at the side thereof next to said forming-face, in applying a side roll or rolls to the side of the work-piece not engaged by said forming-face and with said roll or rolls forcing the work-piece 30 against said forming-face to cause one side of the work-piece within the region bounded by said inner peripheral face to be formed to the shape of said forming-face, for reducing the lateral thickness of the work- 35 piece where desired and forcing the work-piece radially over the peripheral edge of said forming-face to form a rim portion at the die-side of the work-piece, for rolling the side of the work-piece not engaged by 40 said forming-face with a rim portion and for rolling the side of said last-mentioned rim portion, and in subjecting the remainder of said rim portions to the action of rolling rolls whereby the side of the rim portion at 45 the die-side of the work-piece and the outer peripheral face of the entire rim are rolled to desired form.

262. The method of rolling or forming car-wheels or other similar objects from 50 heated ingots, blooms, blanks or other work-pieces, which consists in positioning the work-piece against the forming-face of a die having a central hub-forming cavity and having a diameter equaling that which the inner peripheral face of the rim of the work- 55 piece is to have at the side thereof next to said forming-face, in subjecting the work-piece to rolling pressure or pressures at the side of the work-piece not engaged by said 60 forming-face for forcing metal of the work-piece into said hub-forming cavity to form a hub portion and over the peripheral edge of said forming-face to form a rim portion at the side of the work-piece engaged by 65 said forming-face and for rolling the side

of the work-piece not engaged by said forming-face with a hub portion and a rim portion, in subjecting the opposite sides of the rim formed by said rim portions to rolling pressures whereby the rim is rolled to desired lateral thickness, and in subjecting the outer peripheral face of said rim to rolling pressure or pressures for rolling said face to 70 desired form.

263. The method of rolling or forming 75 car wheels or other circular bodies from heated ingots, blooms, blanks or other work-pieces, which consists in subjecting the work-piece to rolling pressure or pressures against a forming-die having a diameter 80 equaling that which the inner peripheral face of the rim of the work-piece is to have at the side thereof engaged by said die whereby a hub, a web and a rim are formed on the work-piece, and in subjecting the 85 rim portion at all sides thereof excepting the inner peripheral face of the rim at the die side of the work-piece to the action of rolling pressures.

264. The method of rolling or forming 90 car wheels or other circular bodies from heated ingots, blooms, blanks or other work-pieces, which consists in positioning a work-piece against a forming-die adapted to form a portion of one side of the work-piece or 95 car wheel or other body, and in subjecting the remainder of the work-piece or car wheel or other body to the action of rolling pressure or pressures.

265. The method of rolling or forming 100 car-wheels or other circular bodies from heated ingots, blooms, blanks or other work-pieces, which consists in positioning a work-piece against the forming-face of a die having a central hub-forming cavity and a conical outer peripheral edge and having also a 105 diameter equaling that which the inner peripheral face of the car-wheel or other body is to have at the side thereof engaged by said forming-face, in subjecting the 110 work-piece to the action of a side roll or rolls whereby said work-piece is rolled against said forming-face and metal of the work-piece forced into said hub-forming cavity and over the conical peripheral edge 115 of said forming-face, and whereby the work-piece is reduced in thickness between its central and marginal portions from the side thereof not engaged by said forming-face to form a web portion, a hub portion and a 120 rim portion at said last mentioned side and whereby the side of said rim portion at said last-mentioned side of the work-piece is rolled, in subjecting the other side of the rim portion rolled over the conical peripheral edge of said forming-face to rolling pressure, and in subjecting the outer peripheral face of the entire rim to rolling pressure or pressures.

266. The method of rolling or forming 130

- car-wheels or similar bodies from heated ingots, blooms, blanks or other work-pieces, which consists in subjecting the work-piece to the action of axially alined work-supporting axles having means or being formed at adjacent ends thereof to engage the work-piece from opposite sides thereof, in rolling the work-piece over a forming-die whereby a portion of the side of the work-piece or 5 car-wheel or similar body engaged by said die is formed including a hub portion, the inner peripheral face of the rim at said side of the work-piece and an intermediate depressed portion and whereby the other 10 side of said work-piece not engaged by said die is rolled with a hub portion, a rim portion and an intermediate depressed portion, in subjecting the opposite sides of the entire rim to rolling pressures, and in subjecting the outer peripheral face of the entire rim to rolling pressure or pressures 15 conjointly with the rolling pressures applied to the opposite sides of said entire rim.
267. The method of rolling or forming car wheels or similar bodies from heated ingots, blooms, blanks or other work-pieces, which consists in subjecting the work-piece to piercing or penetrating pressures where- 20 by the work-piece is provided at opposite sides with parts of an axial hole, in rolling the work-piece against a forming-die to cause one side of the work-piece to be formed to the shape of said die and the other 25 side of the work-piece to be rolled to desired shape including the rolling of the side of the marginal or rim portion of the work-piece at said other side thereof, and in rolling the peripheral face of the work-piece to 30 the form of a flanged tread or other desired form.
268. The method of rolling or forming car wheels or other similar bodies from heated ingots, blooms, blanks or other work- 35 pieces, which consists in positioning the work-piece against a forming-die adapted to form the hub portion, the web portion and the inner peripheral face of the rim at one side of the work-piece or car wheel or 40 other body, and in subjecting the remainder of the work-piece or car wheel or other body including the opposite sides and the outer peripheral face of the entire rim to the action of rolling pressures.
269. The method of rolling or forming car wheels or other similar bodies from heated ingots, blooms, blanks or other work- 45 pieces, which consists in axially and rotatably supporting the work-piece, in position- 50 ing the work-piece against a forming-die adapted to form a portion of the hub, the web and the inner peripheral face of the rim at one side of the work-piece, and in subjecting the remainder of the work- 55 piece or car wheel or other body to the 60 action of rolling pressures whereby said work-piece is rolled against the side and peripheral face of said die and is also rolled on its remaining surfaces to desired shape.
270. The method of rolling or forming car wheels or other similar bodies from heated ingots, blooms, blanks or other work-pieces, which consists in axially applying or forcing the ends or end supporting means of a pair of rotatable work-supporting axles 70 against or into opposite sides of the work-piece, in rolling the work-piece against a forming-die carried by one of said axles to cause one side of the work-piece including the hub, the web and the inner peripheral 75 face of the rim at said side to be formed to the shape of said die and to cause the remaining surfaces of the work-piece to be rolled to desired form, and in moving said axles lengthwise to cause the work-piece to 80 be dished while retaining the marginal portion of the work-piece in fixed rotatable position.
271. The method of rolling, rerolling, reworking or reforming new or worn heated car wheels or other similar circular bodies or work-pieces, which consists in centrally 85 piercing, penetrating, or centering and supporting the work-piece, in positioning the work-piece against a forming-die having a central hub-forming cavity provided with an outwardly flaring wall, in rolling the work-piece at the side thereof not in contact with said die to cause the central or hub portion of the work-piece at the side thereof in contact with said die to be diametrically compressed within said hub-forming cavity, in 90 rolling the peripheral face of the hub portion of the work-piece at the first-mentioned side thereof to diametrically compress the same, and in rolling, rerolling, reworking or reforming the remainder of the work-piece as and where desired to the desired new form or shape of the new wheel or other new body.
272. The method of rolling or forming car wheels or similar objects from heated ingots, blooms, blanks or other work-pieces, which consists in subjecting the work-piece to the action of piercers or centers, a die and rolls, whereby the work-piece is centrally pierced or penetrated or centered at opposite sides to desired depth or depths and rotatably supported and while so supported is also axially clamped and whereby the work-piece is 110 rolled or formed to undished shape first and is then dished or left undished, as desired.
273. The method of rolling or forming car-wheels or other similar objects from heated ingots, blooms, blanks or other work-pieces, which consists in positioning the work-piece against a forming-die, in axially supporting the work-piece, in supporting said forming-die at the outer side thereof with a die-supporting roll having an edging 125

roll part extending outwardly beyond the peripheral edge of said die and formed to roll in contact with one of the opposite sides of the rim or marginal portion of the work-piece during the operating process, in applying a side roll to the side of the work-piece not in contact with said die to form a portion of the side of the work-piece in contact with said die to the shape of said die, 5 to roll metal of the work-piece over the peripheral edge of said die and against the edging roll part of said die-supporting roll and to roll the side of the work-piece not in contact with said die to desired form, and in 0 applying a face roll to the peripheral face of the work-piece and rolling said side roll and the edging roll part of said die-supporting roll against or in contact with portion of the opposite sides of said face roll. 5

0 274. The method of rolling or forming car wheels or other similar objects from heated ingots, blooms, blanks or other work-pieces, which consists in axially and rotatably supporting the work-piece, in positioning the work-piece against a forming-die, in applying a side roll to the side of the work-piece not in contact with said forming-die whereby the work-piece is rolled against said die to form a portion of the other side of the 0 work-piece to the shape of said die, whereby the work-piece is formed with a hub and a web at the first-mentioned side thereof and whereby metal of the work-piece is extended radially and metal forced outward laterally 5 over the peripheral edge of said die and also outward laterally in the opposite direction to form the rim of the work-piece, in rolling the side of said rim at one side thereof with said side roll, in applying a roll to the other side of said rim to work in opposition to said side roll and roll said other side of said rim and in applying a face roll to the peripheral face of said rim between said other rolls and with said other rolls operating to compress 5 the metal in the rim to uniform density, or practically so.

275. The method of rolling or forming car wheels or other similar bodies from heated ingots, blooms, blanks or other work-pieces, which consists in axially and rotatably supporting the work-piece, in positioning the work-piece against a forming-die having a central hub-forming cavity and a conical peripheral edge, in applying a side 0 roll positioned at one side of the axis of the work-piece to the side of the work-piece not in contact with said forming-die whereby the work-piece is rolled against said die and metal thereof rolled into said hub-forming 5 cavity, whereby the side of the work-piece not in contact with said die is rolled with a hub portion and a web portion and whereby metal of the work-piece is extended radially and forced outward laterally over the peripheral edge of said die and also laterally in

an opposite direction, the said peripheral edge of said die forming the inner peripheral face of the rim inclined at one side thereof and said side roll rolling the inner peripheral face of the rim inclined at the other side thereof, in subjecting the rim at the side thereof rolled over the peripheral edge of said die to the action of an edging roll, in rolling the outer peripheral face of said rim in coaction with said side roll and said edging roll and thereby causing the metal, in the rim to be compressed to uniform density or practically so, and in subjecting the so rolled outer peripheral face and the so rolled inner peripheral face of the rim at another point of the work-piece to rolling pressures to roll said rolled outer peripheral face and said rolled inner peripheral face and thereby cause the metal in said rim to be compressed to maximum density, or approximately so, while maintaining the lateral thickness of the rim to which the same has been rolled during the process by said side roll and said edging roll. 80

276. The method of rolling or forming car wheels or other circular bodies from heated ingots, blooms, blanks or other work-pieces while the work-piece is rotatably supported, which consists in rolling or forming the supported work-piece between a die and a roll 90 located for operation at opposite sides of the work-piece and in subjecting the work-piece to rolling pressures surrounding or partly surrounding the marginal or rim portion of the work-piece in a plane passing laterally therethrough. 100

277. The method of rolling or forming car wheels or similar circular bodies from heated ingots, blooms, blanks or other work-pieces while the work-piece is axially supported, 105 which consists in subjecting the work-piece to the action of a die and a roll or rolls arranged at opposite sides of the work-piece, whereby the work-piece is formed at one side with a hub portion, a web portion and an inner peripheral rim face by means of said die and whereby the other side of the work-piece is rolled with a hub portion, a web portion and an inner peripheral rim face by means of said roll or rolls, and in subjecting the remainder of the rim to rolling pressures whereby the opposite sides and the outer peripheral face of said rim are rolled to desired shape. 110

278. The method of rolling or forming car wheels or similar circular bodies from heated ingots, blooms, blanks or other work-pieces while the work-piece is rotatably supported, which consists in subjecting the supported work-piece to combined roll and die-forging operations, whereby a portion of one side of the work-piece including the hub, the web and the inner peripheral face of the rim at said side is formed by said die and whereby the remaining surfaces of the work-piece or 120 125 130

car-wheel or similar body including the opposite sides and the outer peripheral face of its rim are rolled by the rolls employed in said die-forging operation.

- 5 279. The method of supporting heated work-pieces and rolling or operating upon the same while the work-piece is supported to provide the same with a hub, a web and a rim, which consists in axially piercing, penetrating or centering and supporting the work-piece, in rolling the work-piece against a forming-die adapted to form a portion of one side of the work-piece including the hub, the web and the inner peripheral face of the rim at said side, and in simultaneously therewith rolling the entire opposite side of the work-piece, the outer peripheral face of the rim and the side of the rim at said first-mentioned side of the work-piece to desired shape.
- 20 280. The method of rolling or forming car-wheels or similar circular bodies from heated ingots, blooms, blanks or other work-pieces, which consists in positioning the work-piece against a forming-die and supporting the same, in applying a longitudinally and also laterally movable side roll to the side of the work-piece not in contact with said die to force metal of the work-piece over the peripheral edge of said die by movement or movements of said side roll and to otherwise form the side of the work-piece in contact with said die to the shape of said die and also to roll the side of the work-piece not in contact with said die with a hub portion and a rim portion, in simultaneously therewith applying a face roll or rolls to the outer peripheral face of said rim to roll said peripheral face, and in subjecting the inner peripheral face of said rim portion thus formed by said side roll to the action of a rolling roll to roll said inner peripheral face to desired finished shape.
- 25 281. The method of rolling or forming car-wheels or similar bodies, which consists in positioning the heated work-piece against or into a rotatably supported forming-die and subjecting the work-piece to the action of rolls coöperating with said forming-die to form or roll the work-piece to undished form, and in applying dishing pressure to the central or hub portion of the work-piece to axially move said central or hub portion for dishing the work-piece while the same is being rotated and its marginal or rim portion is rotatably supported and retained against said axial movement.
- 30 282. The method of rolling or forming car wheels or other similar bodies from heated ingots, blooms, blanks or other work-pieces, which consists in rotatably supporting the work-piece and positioning the same with one side thereof against the forming-face of a die having a central hub forming cavity, an annular rim forming groove

coaxial with said cavity and a surrounding wall, in applying a longitudinally and also laterally movable side roll to the side of the work-piece not in contact with said die to force metal of the work-piece into said hub-forming cavity, into said annular rim forming groove and against the inner peripheral face of said surrounding wall, and to roll the side of the work-piece engaged by said side roll with a hub portion, a rim portion and an intermediate depressed or web portion, said hub and rim portions at the last-mentioned side of the work-piece being formed by working metal of the work-piece inwardly and outwardly during longitudinal forward and backward movements of said side roll.

283. The method of rolling or forming car wheels or other similar bodies from heated ingots, blooms, blanks or other work-pieces, which consists in positioning one side of the work-piece against a forming-die having a central hub-forming cavity, an annular rim-forming groove and a surrounding wall, in applying the end or end-supporting means of a pair of axially alined rotatable and axially movable work-supporting axles to opposite sides of the work-piece for axially supporting the same, in applying a longitudinally movable side roll to the side of the work-piece not in contact with said die to force metal of the work-piece into said hub-forming cavity into said annular rim forming groove and against said surrounding wall and to roll the side of the work-piece engaged by said roll with a hub portion, a rim portion and an intermediate depressed or web portion, in rolling the outer side of said rim with said side roll in rolling contact therewith, and in rolling contact with the edge of said surrounding wall, and in moving said work-supporting axles axially together for dishing the work-piece while retaining said die and side roll in rotatable positions.

284. The method of rolling or forming car-wheels or other similar objects from heated ingots, blooms, blanks or other work-pieces, which consists in positioning the work-piece or a portion of the work-piece against or into an axially and rotatably supported forming-die, in subjecting the work-piece or a portion of the work-piece not in contact with said die to the action of rolling pressure or pressures to roll or form the work-piece to desired undished form, and in then dishing the work-piece while the same is being rotated.

285. The method of rolling or forming car-wheels or other similar bodies from heated ingots, blooms, blanks or other work-pieces, which consists in positioning the work-piece against the forming-face of an axially and rotatably supported forming-

- die, in rotating the work-piece and said die by means of a side roll or rolls and simultaneously therewith rolling or forming the work-piece to undished form as desired by 5 means of said die and said side roll or rolls and rolling the peripheral face of the work-piece by means of a peripheral face roll or rolls, and in dishing the work-piece before or during or after the final rolling or forming 10 of the work-piece while the same is being rotated.
286. The method of rolling or forming car-wheels or other similar bodies from heated ingots, blooms, blanks or other work-pieces, which consists in positioning one 15 side of a work-piece against a forming-die having a central hub-forming cavity, an annular rim forming groove and a surrounding wall, in applying the ends or end-supporting 20 means of a pair of axially aligned rotatable work-supporting axles to opposite sides of the work-piece for axially supporting, piercing or penetrating the same, in applying a longitudinally movable side roll 25 situated at one side of the axis of the work-piece to the side of the work-piece not in contact with said die to force metal of the work-piece into said hub-forming cavity, into said annular rim forming groove and 30 against said surrounding wall and to reduce the thickness of the work-piece where desired and during longitudinal movement or movements of said side roll cause metal of the work-piece to flow inwardly toward the 35 ends or end-supporting means of said axles to form a hub portion and outwardly to form a rim portion at the side of the work-piece engaged by said side roll, in rolling the outer side of said rim portion even 40 with the outer edge of said surrounding wall and the adjoining inner peripheral face of said rim portion to inclined form whereby the metal in the rim is uniformly compressed, in applying a side roll situated at 45 the other side of the axis of the work-piece at the side thereof not in contact with said side die and rolling the same in contact with the rolled inner peripheral face of said rim portion to change the inclination or 50 shape of said rolled inner peripheral face and to roll the metal in the rim of the work-piece to maximum density or approximately so.
287. The method of rolling or forming 55 car-wheels or similar circular objects from heated ingots, blooms, blanks or other work-pieces, which consists in positioning the work-piece against a rotatably supported forming-die, in subjecting the so positioned work-piece to the action of a side roll or 60 rolls and a peripheral face roll or rolls operating in conjunction with said die, whereby the work-piece and die are rotated and the work-piece rolled or formed to undished 65 form as desired, and in subjecting the work-

piece while the same is rotated to the action of dishing pressure or pressures which dish the work-piece to desired dish of the car-wheel or similar body.

288. The method of rolling or forming car-wheels or other circular bodies from heated ingots, blooms, blanks or other work-pieces, which consists in positioning the work-piece against a rotatably supported forming-die of larger diameter than said work-piece, in 70 subjecting the so positioned work-piece to the action of rolls operating in conjunction with said die, whereby the work-piece and die are rotated and the work-piece rolled or formed to undished form as desired, and in 75 dishing the work-piece while the same is rotated by at least one of said rolls.

289. The method of rolling or forming car-wheels or other circular bodies from heated ingots, blooms, blanks or other work-pieces, which consists in positioning the work-piece against a rotatably supported forming-die of smaller diameter than said work-piece, in subjecting the so positioned work-piece to the action of rolls operating 80 in conjunction with said die to roll or form the work-piece to undished form as desired, and in dishing the work-piece while the 85 same is being rotated.

290. The method of rolling or forming car-wheels or other circular objects from heated ingots, blooms, blanks or other work-pieces, which consists in positioning a work-piece against a forming-die adapted to form a portion of one side of the car-wheel or 90 other circular object, in subjecting the remainder of the work-piece or car-wheel or other object to the action of rolling pressures coöperating with said forming-die to roll or form said work-piece or car-wheel 100 or other object to desired form with an undished web, and in exerting pressure axially in one direction to dish the work-piece or car-wheel or other object while retaining the marginal or rim portion of the same between 110 said forming-die and the rolling pressure elements.

291. The method of rolling or forming car-wheels or other circular objects from heated ingots, blooms, blanks or other work-pieces, which consists in rolling or forming the work-piece with an undished web by means of a forming-die and a rolling roll or rolls, and in dishing the work-piece thus formed while retained between said die and 120 said roll or rolls.

292. The method of rolling or forming car-wheels or other circular objects from heated ingots, blooms, blanks or other work-pieces, which consists in positioning a work-piece against a forming-die and in rolling the work-piece against said die to roll or form the work-piece to desired undished form, and in dishing the work-piece while 125 retained between said forming-die and the 130

rolling elements employed to roll the work-piece against said die.

293. The method of rolling or forming car-wheels or other circular objects from heated ingots, blooms, blanks or other work-pieces, which consists in rolling or forming the work-piece to desired undished form by means of a forming-die and a roll or rolls, and in axially moving the portion of the 10 work-piece surrounded by the marginal or rim portion thereof while retaining said marginal or rim portion in fixed rotatable position with said die and roll or rolls.

294. The method of rolling or forming car-wheels or other circular objects in an apparatus or mill from heated ingots, blooms, blanks or other work-pieces, which consists in rolling or forming the work-piece to desired undished form by means of a 15 forming-die and a roll or rolls, and in dishing the work-piece thus formed before removing the same from the apparatus or mill.

295. The method of rolling or forming car-wheels or other circular objects from heated ingots, blooms, blanks or other work-pieces, which consists in rolling the work-piece into the form of an undished car-wheel between a forming-die and a roll or rolls, and in dishing the 20 undished car-wheel thus rolled or formed before removing the same from the apparatus or mill.

296. The method of rolling or forming car-wheels or other circular objects from heated ingots, blooms, blanks or other work-pieces, which consists in supporting the work-piece and positioning or forcing the same against a forming-die, in applying a roll or rolls to the work-piece and therewith roll or force the latter against said die and 30 roll or form the work-piece into a car-wheel or other circular object having a hub, an undished web and a rim, and in retaining the marginal or rim portion of work-piece in fixed rotatable position while axially moving the central portion of the work-piece to cause dishing of said undished web.

297. The method of rolling or forming car-wheels or other circular objects from heated ingots, blooms, blanks or other work-pieces, which consists in axially applying the ends or end-supporting means of a pair of aligned work-supporting axles to opposite sides of the work-piece while positioning the work-piece against a forming-die, in applying rolling rolls to the work-piece and therewith force or roll the latter against said die and roll or form the work-piece into a car-wheel or other object having a hub, an undished web and a rim, and in axially moving said work-supporting axles to dish the web of the car-wheel or other object while retaining the marginal portion thereof in fixed rotatable position between said rolls and the marginal portion of said die.

298. The method of rolling or forming

car-wheels or other circular objects having each a web and an annular rim extending from opposite sides of said web from heated ingots, blooms, blanks or other work-pieces, which consists in rolling or forming the 70 work-piece by means of a forming-die and rolling rolls to roll or form the web to desired thickness and undished form and the inner peripheral faces of the rim as desired, to roll said rim to desired lateral thickness 75 and the outer peripheral face thereof to rudimentary form and to roll said rim including its outer peripheral face to finished form, and in dishing the web of the work-piece while the same is rotated, or leaving 80 said web in undished form.

299. The method of rolling or forming car-wheels or other circular objects having each a central portion including a web and having a rim from heated ingots, blooms, 85 blanks or other work-pieces, which consists in rolling or forming the work-piece by means of a rotatable forming-die and rolling rolls whereby the central portion of the work-piece is rolled or formed to undished 90 form as desired and the inner peripheral faces of the rim rolled or formed as desired, whereby the rim is rolled to desired lateral thickness and the outer peripheral face thereof is rolled first to rudimentary form 95 and is then rolled to finished form, and in dishing the work-piece before or during or after the rolling of said rim to finished form.

300. The method of rolling or forming car-wheels or other circular objects having 100 a rim extending at opposite sides thereof from heated ingots, blooms, blanks or other work-pieces, which consists in rolling or forming the work-piece by means of a forming-die and rolling rolls situated at one side 105 of the axis of said die for rolling and forming the inner peripheral faces of said rim sufficiently inclined, substantially as described, for rolling the outer peripheral face to rudimentary form and for rolling the opposite sides of said rim to finish, and in rolling said rim at another point to finished form while maintaining the lateral thickness thereof with at least two of said first-mentioned rolling rolls.

301. The method of rolling or forming car-wheels or other circular objects having a rim extending at opposite sides thereof from heated ingots, blooms, blanks or other work-pieces, which consists in rolling or 120 forming the work-piece by means of a forming-die and rolling rolls situated at one side of the axis of said die for rolling or forming the inner peripheral face of said rim at one side of the work-piece with said die to sufficiently inclined finished form and for rolling the inner peripheral face of said rim at the other side of the work-piece to sufficiently inclined form substantially as described for rolling opposite sides of the rim 125 130

and governing the lateral thickness of said rim and for rolling the outer peripheral face thereof to rudimentary form, in applying rolling rolls situated at the other side or at 5 another side of the axis of said die for rolling or forming the inner peripheral face of the rim at said other side of the work-piece and the outer peripheral face of said rim to finish while maintaining the lateral thickness 10 of said rim to which said rim has been rolled with said first-mentioned rolling rolls.

302. The method of rolling or forming car-wheels or other circular objects having 15 a central portion including a web and having a rim extending from opposite sides of said web from heated ingots, blooms, blanks or other work-pieces, which consists in rolling or forming the work-piece by 20 means of a forming-die and rolls exerting pressures in different directions to roll or form the inner peripheral faces of the rim sufficiently inclined, substantially as and for the purpose described, to roll said rim to 25 the desired lateral thickness and to roll the peripheral face thereof to rudimentary form.

303. The method of rolling or forming car-wheels or other circular objects, which 30 consists in rolling or forming a work-piece by means of a forming-die and a rolling roll or rolls adapted for exerting pressure against the work-piece in different directions to roll or form the central portion 35 of the work-piece with a hub and web and to roll or form the rim of the work-piece with its inner peripheral faces sufficiently inclined, substantially as and for the purpose described, to roll said rim to 40 desired lateral thickness and to roll the outer peripheral face thereof first to beaked form and then to finished form.

304. The method of rolling or forming car-wheels or other circular objects having 45 each a central portion including a web and having a rim extending from opposite sides of said web from heated ingots, blooms, blanks or other work-pieces, which consists in rolling or forming the work-piece by 50 means of a forming-die and rolling rolls including a side roll or rolls situated at one side of the axis of said die for rolling or forming said central portion to undished form as desired and the inner peripheral 55 faces of said rim as desired, for rolling the outer peripheral face of said rim to rudimentary form and for rolling said rim to desired lateral thickness, in rolling said rim at another point thereof to finished form 60 while maintaining the lateral thickness thereof with the side rolls of said first-mentioned rolling rolls or with said forming-die and the side roll of said first-mentioned rolling rolls, and in dishing the work piece 65 before or during or after the rolling of said

rim to finished form, or leaving the work-piece in undished form.

305. The method of rolling or forming car-wheels or other circular objects, which consists in rolling or forming a heated 70 work-piece by means of a forming-die and rolling rolls exerting pressures in different directions to roll or form the work-piece into a car-wheel or other circular object having a web and an annular rim surrounding said web and to roll or form the inner peripheral faces of said rim sufficiently inclined to cause the metal therein during the operating process to flow in the proper direction to be compressed to uniform density or practically so substantially as described. 75

306. The method of rolling or forming car wheels or other circular bodies, which consists in rolling a work-piece against a 80 forming die with a side roll or rolls, whereby one side of the work-piece is formed by said die and the other side of the work-piece is rolled by said side roll or rolls and whereby the work-piece is rolled or formed to undished shape, in resisting the pressure or pressures applied to the work-piece by said side roll or rolls with a die-supporting roll or rolls marginally engaging said die, in rolling the peripheral face of the work-piece 90 with a face roll or rolls, and in dishing the work-piece while the same is rotated. 95

307. The method of rolling or forming car-wheels or other similar objects from heated blanks or other work-pieces, which 100 consists in positioning or placing the work-piece against a forming-die, in subjecting the so positioned work-piece to the action of rolls operating in conjunction with said forming die whereby the work-piece is rolled 105 or formed into the form of an undished car-wheel or other similar undished object, and in dishing the work-piece or car-wheel or other object, or leaving the same in undished form. 110

308. The method of rolling or forming car-wheels or other circular objects, which consists in positioning a heated work-piece against a forming-die having a pair of die-supporting rolls in rolling contact with the 115 outer side of said die and at opposite sides of the axis of said die and in successively applying a pair of rolling rolls and a pair of peripheral face rolls to the so positioned work-piece in the lateral plane or planes 120 of said die-supporting rolls whereby the side of the work-piece in contact with said die is formed to desired and undished shape by said die and simultaneously therewith the other side of the work-piece is rolled to undished shape and partly finished with one of said rolling rolls, and the peripheral face of the work-piece is rolled to beaked or rudimentary form by one of said face rolls and whereby said other side of the work-piece 125 130

is rolled to finished shape with the other of
said rolling rolls and the so rudimentarily
formed peripheral face of the work-piece is
rolled to finished form with said other face
5 roll, and in dishing the work-piece or car-
wheel or other object, or leaving the same
in undished shape.

In testimony whereof, I have hereunto set
my hand.

LOUIS F. DIETER.
